UNITED STATES PATENT OFFICE.

ALFRED H. DYSON, OF MONTCLAIR, NEW JERSEY, ASSIGNEE TO WESTERN ELECTRIC COMPANY, INCORPORATED, OF NEW YORK, N. Y., A CORPORATION OF NEW YORK.

TELEPHONE-EXCHANGE SYSTEM.

1,352,660.

Specification of Letters Patent. Patented Sept. 14, 1920.

Application filed December 8, 1915. Serial No. 65,804.

To all whom it may concern.

Be it known that I, ALFRED H. DYSON, a citizen of the United States, residing at Montclair, in the county of Essex and State 5 of New Jersey, have invented certain new and useful Improvements in Telephone-Exchange Systems, of which the following is a full, clear, concise, and exact description.

The present invention relates generally to 10 improvements in telephone exchange systems, and has to do more particularly with multi-office systems in which selective switching devices are employed at the central offices arranged to be automatically and 15 directively actuated for connecting calling subscribers' lines with desired called subscribers' lines; an object of the invention being to provide means comprising improved arrangements of circuits and apparatus as herein illustrated, described and claimed.

The present embodiment of the features of the invention is illustrated and described as applied to multi-office automatic call distributing telephone exchange systems, and 25 comprises improved means whereby connections between subscribers of various classes, having lines terminating in a central office equipped as a call distributing 30 office, may be expeditiously and efficiently connected in conversational circuit with other desired subscribers of various classes and having lines terminating in the same central office or in other central offices similarly equipped.

There are also herein illustrated, described and claimed as features of this invention improved means for bringing about the establishment of conversational circuit 40 connections between subscribers having lines terminating in offices equipped as automatic call distributing offices and subscribers having lines which lead to and terminate in so-called manual offices.

It will be apparent to those skilled in the art that changes and modifications of the various features of the invention disclosed and hereinafter described are capable of use in varying environments. It is, therefore, 45 fore, not intended that the claims be given an interpretation specific only to the herein illustrated embodiment of the invention,

but it is desired and intended that they be considered of such comprehension as to apply with equal force to other structures 55 when embodied therein.

The many features and advantages of the invention will be better understood upon reference to the following detailed description taken in connection with the accompanying drawings, in which—

Figures 1, 2 and 3 illustrate the central office circuits of subscribers' lines of various classes equipped with substation apparatus of any of the usual and well-known arrangements of the corresponding classes.

Fig. 4 illustrates circuits of the allotters and the line finders employed for automatically extending connection of calling subscribers' lines to connection with the connecting circuits.

Fig. 5 shows the circuits of the connecting circuit selectors permanently electrically linked with the line finders of Fig. 4.

Fig. 6 shows the circuits of the secondary 75 connecting circuit selectors employed to automatically extend the connections of calling lines to connection with the connecting circuits appearing before operators of a second group.

Fig. 7, Parts 1 and 2, illustrates the arrangement of the circuits of the connecting circuits, including circuits of the means for indicating the class of calling substations when brought into connection with the connecting circuits, and also circuits of various keys and other controlling means for enabling the operators to rapidly and properly perform the operations required in the establishment and the control of connections 85 between the calling and called subscribers.

Fig. 8 illustrates the circuits of the allotters, and the connecting circuit finders which are utilized to bring about the automatic connection of the impulse transmitters 95 with the connecting circuits.

Fig. 9, Parts 1 and 2, illustrates the circuits of the recording keys associated with and common to the connecting circuits of an operator's position, together with one of 100 a plurality of sets of the impulse transmitters which are utilized for controlling the operation of the directively actuated switches used to extend the connections

of the lines of the calling substations from the connecting circuits of Fig. 7 to the lines of desired called substations.

Fig. 10 shows the circuits of the district 5 selectors individual to and electrically linked with the connecting circuits.

Fig. 11 shows circuits of the local incoming 10 selectors which are utilized in the establishment of the connections between lines of calling substations and the lines of called substations which terminate in the same automatic call distributing central office.

Fig. 12 shows the circuits of the herein 15 designated hundreds selectors utilized for extending the connections from the incoming selecters to the final selectors.

Fig. 13 illustrates the circuits of the final 20 selectors to the passive contacts of which are connected the called terminals of the lines of the various classes, as indicated in Figs. 1, 2 and 3.

Fig. 14 shows the circuits of the office 25 selector switches which are utilized for extending the connections from the district 5 selectors to the called subscribers' lines which terminate in offices other than the lines of the calling subscribers.

Fig. 15, parts 1 and 2, illustrates the 30 circuits of the trunk lines connecting the various offices equipped as automatic call distributing offices and the circuits of the herein designated interoffice incoming selecters.

Fig. 16 illustrates the circuits of the trunk 35 lines leading from the automatic call distributing offices to the manual offices and the circuits of the means employed at the manual offices for completing connections between the lines of the calling substations terminating in automatic call distributing 40 offices with the lines of called substations terminating in the manual offices.

Fig. 17 illustrates circuits of the herein 45 designated cord finders, circuits of the allotters and the circuits of the decimal distributors which are utilized for indicating to the operators at the manual offices the numerical numbers of called manual subscribers with which connection is to be established.

Fig. 18 shows the circuits of the decimal 50 registers and the indicator lamps for indicating to the operators at the manual offices the numerical numbers of called manual substations.

Fig. 19, Parts 1 and 2, illustrates the 55 circuits of the trunk lines connecting the manual offices with the automatic call distributing offices, together with the herein designated manual incoming selector switches 60 utilized for establishing connections between the lines of calling substations terminating in manual offices and the lines of called substations terminating in the automatic call distributing offices.

Fig. 20 illustrates the circuits of the herein 65

in designated manual incoming trunk finder switches which are employed at the automatic call distributing offices for establishing connections between calling substation lines terminating in the manual offices and 70 called substation lines terminating in the automatic call distributing offices.

Fig. 21, Parts 1 and 2, illustrates the circuits of the recording keys, the allotters, recorders and impulse transmitter employed 75 for extending the calling substation lines terminating in manual offices to connection with the lines of called substations terminating in automatic call distributing offices.

Figs. 22 to 33 inclusive illustrate a section 80 of the impulse transmitters which are employed for controlling the directive selective operation of the various selector switches.

Figs. 34, 35 and 36 are views of a mechanical 85 arrangement of the recorders which are associated with the recording keys and with the impulse transmitters utilized by the operators for controlling the selective operation of the directly actuated selector 90 switches employed in establishing connections between the lines of calling substations terminating in manual offices and the lines of substations, as called substations, terminating in the automatic call distributing 95 offices.

Fig. 37 is a diagram illustrating the arrangement 100 of the circuit diagrams and is provided as an assistance in describing the invention.

General arrangement of system.

Referring now in general to the arrangement 105 of the system of the invention and more particularly to the circuits illustrated in Figs. 1 to 21 inclusive, which may be more readily followed by placing the drawings as indicated in Fig. 37. In order that the drawings may be simplified as far as possible, the complete circuits necessary in 110 establishing only a single connection from a calling to a called substation are illustrated.

The substation lines of the system of the invention as illustrated are divided, first, 115 into a plurality of sections termed "districts," and second, each district section is divided into a plurality of sections termed "offices." Each office section may comprise 10,000 substations and the lines of each such 120 section may terminate in a central office located at a distance from the central offices in which terminate the lines of each of the other office sections.

The substation lines of each office section, 125 as calling lines, may be divided into major groups according to classes. Each major group is divided into as many secondary groups of 300 lines each as the major group contains multiples of 300, and each second- 130

ary group divided into twenty minor groups of fifteen lines each.

The substation lines of each office section, as called lines, are divided into (a) ten groups herein termed "thousands groups," each of which may comprise 1,000 substations; (b) each thousands group is divided into five groups herein termed "hundreds groups," each of which may comprise 200 substations; (c) each hundreds group is divided into two groups, each comprising a maximum of 100 substations; (d) each group of 100 is divided into ten groups termed "tens groups," each comprising not 15 to exceed ten substations.

The arrangement of the lines of the multi-party class is such that the called terminals of each such line is multiply connected to the passive contacts of the final selectors 20 of a hundreds group in as many thousands groups as there are substations connected therewith.

The arrangement illustrated for intra-office connections includes a calling substation connected by line conductors to its line circuit apparatus located at its central office, which may be as indicated in Figs. 1, 2 and 3, an allotter and line finder (Fig. 4), a connecting circuit selector (Fig. 5) which is connected as a pair with the line finder of Fig. 4, a secondary connecting circuit selector (Fig. 6), a connecting circuit (Fig. 7, Parts 1 and 2), an allotter and connecting circuit finder (Fig. 8) having access to the secondary group of connecting circuits allotted to an operator's position (Fig. 7, Parts 1 and 2). With each such connecting circuit finder is associated an impulse transmitter as illustrated in Fig. 9, Parts 1 and 2, and 35 associated with the impulse transmitters of each operator's position are a plurality of sets of recording keys (also illustrated in Fig. 9, Parts 1 and 2), a district selector (Fig. 10) which is permanently electrically connected with the connecting circuit of Fig. 7, a local incoming selector (Fig. 11), a hundreds selector (Fig. 12), final selector (Fig. 14), and called line circuits as shown in Figs. 1, 2 and 3.

When connection is to be established between a calling substation, the line of which terminates in one automatic call distributing central office, and the line of a called substation which terminates in some other automatic call distributing office, the local incoming selector of Fig. 11 is dispensed with and interposed instead therefor is the office selector of Fig. 14, the trunk line circuit and the inter-office incoming selector of Fig. 15, Parts 1 and 2.

Should connection between a calling substation of a line terminating in an automatic call distributing office be desired with a called substation of a line terminating in a

manual office, then neither the local incoming selector (Fig. 11) nor the inter-office incoming selector (Fig. 15) will be utilized, but the connection will extend from the passive contacts of a district selector, through an office selector and thence over a trunk line to the manual office, and there terminate in a plug switch adapted to be connected with a multiple jack of the line of the called substation as shown in Fig. 16.

Common to the said plug switch terminals of the trunk lines allotted to an operator at the manual offices there is provided an allotter and a plurality of cord finders (Fig. 17), with each of which is associated controlling devices which are arranged to be operated under the control of the impulse transmitters of Fig. 9, Parts 1 and 2, to indicate to the operators at the manual offices the numerical designations of the called substations and is evidenced on the indicators 85 shown in Fig. 18.

For establishing connections between calling substations having lines terminating in manual offices and called substations having lines terminating in automatic call distributing offices, the trunk lines, as illustrated in Fig. 19, Part 1, and the manual incoming trunk selectors, Fig. 19, Part 2, are employed. There is provided, associated with and common to each group of these trunk lines allotted to an operator, an allotter and a plurality of manual incoming trunk finder switches, as illustrated in Fig. 20, with each of which said finder switches is associated an impulse transmitter, as 95 illustrated in Fig. 21, Parts 1 and 2. Common to the trunk circuits of an operator's position and also illustrated in Fig. 21, Parts 1 and 2, are the recording keys and recorders which are employed to control the setting 105 operations of the impulse transmitters.

The circuits and apparatus illustrated having been described in general, they will now be more particularly referred to.

110 Specific arrangement of lines and line finders.

The substation equipments are not illustrated, as they may be of any of the well-known standard arrangements adapted for the particular classes. The lines of each include at the central office a line relay LR, a cutoff relay CO, a line signal lamp LL (for multi-party lines—an additional lamp for each substation of the line), and if the line be of the central office metered service class, 115 also, a message registered MR.

As previously stated, the substation lines, as calling lines, may be divided into secondary groups of 300, and for each such group there is provided a plurality of line finders (Fig. 125 4), each comprising 300 sets of passive contacts 411, 412, 413, 414 to which are multiply connected the calling terminals of the

lines of the associated secondary group. These sets of passive contacts are divided into as many minor groups or rows of fifteen contact sets each as the secondary group contains multiples of fifteen, so that in the operation of the finder switches of Fig. 4, there brushes W^1 , W^2 , W^3 , W^4 , W^5 are first operated to select the row of passive contacts containing the multiply connected terminals of the line of a calling substation and brushes W^2 , W^3 , W^4 , W^5 thereafter operated to select the desired terminals of the selected row.

For controlling the selection of the minor group or row of passive contacts containing the terminals of the line of a calling substation, there is provided for each line finder a row of passive contacts 415 coöperating with brush W^1 , there being as many contacts 415 for each line finder as there are rows or minor groups of contacts 411, 412, 413, 414, of which there are twenty. Therefore, it will be seen that the calling terminals of the lines of each secondary group of 300 is further divided into twenty minor groups of fifteen each. For each minor group of calling terminals of fifteen lines, a group relay GBC is provided, multiply connected by common conductor 416 to its fifteen line circuits and its normal contact multiply connected by conductor 417 to the corresponding contacts 415.

For each secondary group of 300 lines, as calling lines, there is provided an allotter, as illustrated in Fig. 4, adapted upon initiation of a call over any of its associated lines to cause an idle line finder (Fig. 4) and its paired connecting circuit selector (Fig. 5) to be simultaneously started on their selecting operations, the line finder to find a calling line and the connecting circuit selector to select a connecting circuit. These allotters are of a well-known rotary switch construction, each adapted to move its brushes W^6 , W^7 forwardly only. As these allotters are each common to 300 lines and the associated plurality of line finders and connecting circuit selectors, there are as many sets of bank contacts 418, 419 provided therefor as there are line finders allotted to the group. The coöperating brushes W^6 , W^7 are insulatingly mounted upon a shaft adapted to be positioned by a step-by-step movement effected by a well-known ratchet and pawl arrangement controlled by the motor magnet MM, which is in turn controlled by a relay T.

An allotter being common to a secondary group of 300 lines, the switch starting conductor 420 is multiply connected to a contact of each of the group relays GBC of the twenty minor groups of the associated secondary group, so that any of the substations of the lines thereof is adapted when calling to effect the starting operations of each pair of associated line finders and con-

necting circuit selectors (Figs. 4 and 5), by means of the common conductor 420.

Before proceeding further with the description of the circuits, it is believed that their operation will be more readily understood by referring to the type of finder and selector switch mechanism employed for illustrating the features of this invention, which is of the two-dimension type, and structurally generally such as shown in U. S. 70 75 patent to William Kaisling, 1,131,140, dated March 9, 1915, but is modified somewhat from the specific structure illustrated in the patent referred to in that the number of rows or groups of passive or bank contacts, the 80 number of sets of such contacts per row, and the number of contacts per set, vary according to the particular uses. The specific arrangements herein employed further differ from the structure of the mentioned patent 85 in that the automatically actuated ones of the motor magnets employ a source of direct current in conjunction with a well-known interrupter arrangement of the art. The structure specifically differs also from the patent 90 referred to in that there is added what are herein termed "primary over-run contacts" and "secondary overrun contacts", which are actuated during the operation of the 95 various switches and for the purposes which will hereinafter be fully explained. For a more complete understanding of the mechanical structure of these switches, reference may be had to the identified patent.

Referring again to the line finder (Fig. 100 4), for adjusting the brushes W^1 , W^2 , W^3 , W^4 , W^5 in their primary selecting operation to select a row of passive contacts, a primary magnet PM is provided, being adapted to act upon ratchet and shaft mechanism to move the brushes W^1 , W^2 , W^3 , W^4 , W^5 step by step to any of the groups of contacts 411, 412, 413, 414, the movement being controlled through the group contacts 415 and coöperating brush W^1 .

For controlling magnet PM, a primary test relay PT is provided, while a secondary magnet SM and an associated test relay ST are provided for controlling the secondary selecting movement of brushes W^2 , W^3 , W^4 , W^5 to connection with the passive contacts 411, 412, 413, 414. The primary off-normal contacts PON are adapted to be moved to their alternate position upon the first primary step of the brushes, while secondary off-normal contact SON is adapted to be moved to the alternate position upon the first secondary step of the brushes. The contact of POR is closed if the brushes in their primary setting operation are moved 110 one step beyond their last row of passive contacts, and contact SOR is closed upon the movement of the brushes W^2 , W^3 , W^4 , W^5 one step beyond the last contact of a selected row. Release relay RR controls the 115 120 125 130 135 140 145 150 155 160 165 170 175 180

restoration of the line finder (Fig. 4), in a manner to be described hereinafter.

General arrangement of selector switches.

The connecting circuit selectors (Fig. 5), the secondary connecting circuit selectors (Fig. 6), the connecting circuit finders (Fig. 8), the cord finders, (Fig. 17), and the manual incoming trunk finders (Fig. 10-20), each comprise a structure similar to that of the line finder (Fig. 4), in that they are provided with a plurality of rows of sets of passive contacts, group and line selecting brushes, test relays and motor magnets, primary off-normal and secondary off-normal contacts, primary over-run and secondary over-run contacts functioning as in the line finder of Fig. 4 and bearing similar reference characters but with a different suffix 20 added for each of the different switches.

The district selectors (Fig. 10), the local incoming selectors (Fig. 11), the group selectors (Fig. 12), the office selectors (Fig. 14), the interoffice incoming selectors (Fig. 15), and the manual incoming trunk selectors (Fig. 19), are structurally similar to the line finder of Fig. 4 but differ therefrom in that the primary selecting operation of the brushes is directly controlled 30 through the medium of impulses transmitted thereto operating to actuate the primary motor magnets to move the brushes to a desired group. Means are provided for, under certain conditions, thereafter causing 35 the brushes to automatically continue the primary selecting operation followed by the automatic actuation of the brushes in a secondary direction in response to the automatic actuation of the secondary motor 40 magnets. Like parts of these switches bear reference characters similar to those of the line finder of Fig. 4, but with a different suffix for like parts of the switches of the different classes.

The final selectors of Fig. 18 are also structurally similar to the selector switches mentioned and likewise similar to the patent referred to, but differ therefrom in that in the present embodiment of this invention 50 there is a specific number of 200 sets of passive contact terminals divided into twenty rows or groups of ten sets of contacts each, to which are directly multiply connected the called terminals of the substation lines. 55 The selecting operations are directly controlled by impulses transmitted to the motor magnets from the impulse transmitters at the operators' positions. They are adapted to have their brushes directly actuated in 60 the primary selecting direction to select a group of terminals which may comprise two or more rows or minor groups, in which event the brushes are thereafter automatically actuated in the primary direction to 65 select a minor group containing a selectable

set of contacts, and thereafter automatically actuated in the secondary selecting direction to select the first encountered set of selectable contacts. Or the brushes may be directly actuated in the primary direction to a desired row or minor group of sets of contacts, under the control of impulses transmitted thereto from the impulse transmitters, and then automatically actuated in the secondary selecting direction to 70 connection with a set of selectable contacts, terminals of a substation line. Or the brushes of these switches may be directly actuated in the primary selecting direction followed by the directive actuation in the 75 secondary selecting direction to connection with a particular set of passive contacts, terminals of a particular line of a called substation terminating thereon. The various parts of the final selectors, functioning 80 similarly to like parts of the line finders (Fig. 4), bear similar designating characters but with distinguishing exponents.

*Specific arrangement of connecting circuit 90
selectors.*

Considering now the connecting circuit selectors (Fig. 5) and the secondary connecting circuit selectors (Fig. 6), and having particular reference to the connections 95 of the terminals of the connecting circuits of Fig. 7 thereto, it will be obvious to those skilled in the art that many arrangements may, without departing from the scope of this invention, be employed. In order that 100 the disclosure may be simplified, only the following one arrangement will be illustrated.

The connecting circuits are divided into what are herein termed "major groups" of 105 450 each, and each of the major groups subdivided into fifteen secondary groups of thirty each, the circuits of each secondary group appearing before a different operator; that is, the connecting circuits of each of the 110 major groups appear before a different team of fifteen operators.

In order that the connecting circuits may be selected by the connecting circuit selectors and the secondary connecting circuit 115 selectors without effective delay, the calling terminals of each secondary group are subdivided into two minor groups, each comprising fifteen. One of the minor groups of each of the secondary groups of a major 120 group is multiply connected to the passive contacts 502, 503, 504 and 505 of a plurality of connecting circuit selectors (Fig. 5), each to a different row or minor group of passive contacts, and the other minor group of each 125 secondary group of the same major group in like manner is multiply connected to a second plurality of connecting circuit selectors. For each row or minor group of passive contacts, multiple terminals of connecting cir- 130

cuits, there is provided a contact 501 herein termed "group test contact."

In addition to the fifteen rows of passive contacts, 502 to 505 inclusive, multiple terminals of connecting circuits, each connecting circuit selector is provided with an additional row of fifteen sets of passive contacts, to each of which are multiply connected selective terminals of a secondary connecting circuit selector (Fig. 6), which, as stated, is similar to the connecting circuit selectors, and for the purpose of illustration is provided with fifteen rows or minor groups of fifteen sets each of passive contacts 602, 603, 604, 605. The passive contacts of each row of the secondary connecting circuit selectors are multiply connected to the selective terminals of a minor group of a secondary group of a second major group of connecting circuits appearing before a second team of fifteen operators. For controlling the selection of each of the rows or minor groups of passive contacts of the secondary connecting circuit selectors, there is provided for each row a passive contact 601 herein termed "group test contact."

The arrangement is such that upon actuation of a connecting circuit selector, responsive to the initiation of a call, the brushes W^8 , W^9 , W^{10} , W^{11} , W^{12} are automatically rotated from normal, in their primary selecting direction, to the first row or minor group of contacts, terminals of connecting circuits of a minor group, appearing before an operator of a team of fifteen operators, and if all such connecting circuits be at the time busy, or if the operator before whom they appear be busy, then the automatic rotation of the brushes W^8 to W^{12} inclusive, will be continued to the second sub-group, and so on, until the brush W^8 engages the contact 501 corresponding to a minor group in which is included a set of passive contacts, to which is multiply connected a connecting circuit then idle and appearing before an operator then idle, when the primary selective operation of the connecting circuit selector will terminate and the brushes W^8 , W^{10} , W^{11} and W^{12} thereupon will be automatically rotated into and out of engagement with their corresponding terminals 502, 503, 504 and 505 until a set connected with an idle connecting circuit is engaged, when the brushes will be brought to rest in engagement therewith and the calling line thus extended to connection with an idle connecting circuit.

Should all of the connecting circuits terminating on the passive contacts of a connecting circuit selector be, at the time of the operation of the selector in its attempt to select an idle one of such circuits, busy, or should all of the operators before whom such connecting circuits appear be busy, or if all 65 of the connecting circuits of the major group

appearing before some of the operators be busy and the remaining connecting circuits appear before operators which are busy, then the brushes of the connecting circuit selectors will be automatically rotated in the 70 primary selecting direction beyond the last row of contacts, which are multiple terminals of connecting circuits, and come to rest before the last row of contacts, terminals of secondary connecting circuit selectors, 75 whereupon the brushes W^8 , W^{10} , W^{11} , W^{12} will be automatically rotated into and out of engagement with the sets of passive contacts of the row, until a set connected with an idle secondary connecting circuit selector 80 is engaged, when they will be brought to rest and the line of the calling substation extended to said selected secondary connecting circuit selector.

Responsive to the selection of a secondary 85 connecting circuit selector, the brushes W^{13} , W^{14} , W^{15} , W^{16} and W^{17} of such selector are automatically rotated in their primary selecting direction until a row of contacts 602, 603, 604 and 605, terminals of connecting circuits of a minor group of a secondary group of a second major group appearing before a second team of fifteen operators, containing the terminals of a connecting circuit then 95 idle and appearing before an operator then idle, are reached, when the primary selective rotation of the brushes terminates, whereupon the brushes W^{13} , W^{14} , W^{15} , W^{16} and W^{17} are automatically rotated in their secondary selecting direction, moving step by step into 100 and out of engagement with the sets of contacts 602, 603, 604 and 605, terminals of connecting circuits of the selected minor group, until the terminals 602, 603, 604 and 605 of the first idle one of the connecting circuits 105 of such minor group are engaged; when the brushes come to rest in engagement therewith and thus extend the calling line to connection with such selected connecting circuit.

As previously stated, the substation lines, 110 as calling lines, are divided into major groups according to classes. For each such major group of lines, there is provided associated with the line finders (Fig. 4) and the paired connecting circuit selectors (Fig. 115 5), the interrupters I^1 and I^2 adapted upon extension of the line of a calling substation to connection with a connecting circuit to control the operation of the hereinafter described class of service registers associated 120 with each of the connecting circuits and adapted to control the indication to the operators of the class of the line of the calling substation connected with the associated connecting circuit. These interrupters may be constantly rotating, and the arrangement is such that the brush of I^1 first makes contact with its live segment, following which the brush of I^2 makes and breaks connection successively with its live segments. It will, 125 130

of course, be understood that the number of live segments for the interrupters I^2 differs for each major group of lines. In other words, the interrupters I^2 for each class are provided with a different number of live segments.

Arrangement of connecting circuits.

Referring now to the connecting circuits (Fig. 7, Parts 1 and 2) employed by the operators for establishing and controlling connections of the lines of calling substations with the lines of called substations, the calling terminals of which have been described as being connected to the passive or bank contacts of the connecting circuit selectors (Fig. 5) and the secondary connecting circuit selectors (Fig. 6). These connecting circuits appear before the operators in the form of keys and signal lamps. They may be said to be universal in that they are adapted to establish and control connections of the lines of calling substations of any of the classes with the lines of called substations of any of the classes. They each, therefore, contain devices not necessarily employed in the establishment and control of a connection of the line of a calling substation of any one particular class with the line of a called substation of any one particular class. They are each provided with—

(a) A lamp 701 herein termed "call signal lamp," which when illuminated indicates the selection by and connection of the line of a calling substation with its associated connecting circuit. This lamp, after illumination remains lighted until the number of the called substation has been written by the operator on the recording keys of the position hereinafter to be described. After operation of the recording keys this lamp is extinguished and is not again illuminated during the existence of the connection.

(b) A signaling lamp 702 herein termed "answering supervisory lamp." This lamp after operation of the impulse transmitter to bring about extension of the line of the calling substation to connection with the line of the desired called substation, when illuminated, indicates that the calling subscriber has "hung up." The calling subscriber may, as in manual practice, "flash" this lamp and thus recall the operator. If the calling substation be of the multi-party line class, and if the desired called substation be connected to the same line, then upon completion of the operation of the impulse transmitter this lamp will "flash" and visually indicate to the operator that the called substation is connected to the same line as the calling substation or, in other words, indicate to the operator that the connection is "revertive."

(c) A lamp 703 herein termed "ringing lamp," which during the connection of an

impulse transmitter, hereinafter to be described, with the associated connecting circuit, "dashes" and thereby visually indicates to the operator this condition during the progress of the extension of the line of a calling substation to connection with the line of the desired called substation. After disconnection of the impulse transmitter this lamp burns steadily until the subscriber at the called substation responds. It is thereupon extinguished and is not again illuminated during existence of the connection unless, after the called party "hangs up," it is desired to recall the called substation and the operator resignals or, in other words, rerings the called substation. In such event, this lamp is again illuminated and burns steadily until the called substation again responds.

(d) A signaling lamp 704 herein termed "called supervisory lamp." This lamp when burning steadily indicates to the operator that the called substation then connected with the associated connecting circuit has answered the call and has "hung up." If all available paths to the called terminals of the line of a called substation be busy at time of attempted connection therewith, this lamp will be caused to "flash" in a distinctive manner and thus visually indicate to the operator such condition. Or if the line of the called substation be busy at time of attempted connection therewith, either as a calling line or a called line, this lamp will be caused to "flash" in a manner such as to visually indicate to the operator that the connection with the line of each substation cannot be completed.

The simultaneous steady burning of lamps 703 and 704 visually indicates to the operator that conversation over the calling and called lines then connected with the associated connecting circuit has been terminated and that the two lines should be disconnected. That is, the apparatus used in establishing the connection should be restored to normal.

(e) A key 705 herein termed "holding key." This key is "locking" and when operated will cause the release of the line of a calling substation connected with the associated connecting circuit but will hold the line finder, connecting circuit selector and, if used, the secondary connecting selector in their actuated positions. This key is employed for completing connections termed "busies"; in other words, if at the time of attempted connection of the line of a calling substation with the line of a substation, as a called substation, such last mentioned line be busy, and it be desired to repeat the attempt to establish the connection, the operator may hold the finder and selector switches in their actuated position until such time as she is able to complete the de-

sired connection, when by restoring this key the calling line is again placed in connection with the connecting circuit. This arrangement is also found desirable in certain cases 5 of defective operation of the apparatus.

(f) A key 706 herein termed "disconnect and collect" key. This key when actuated from normal will cause disconnection of the lines of the calling and called substations 10 from the associated connecting circuit. If the calling substation be equipped as a pay-station or be provided with a substation message register, or if the line of the calling substation be provided with a central office 15 message register, the actuation of this key from normal will, if the called substation has responded and "hung up," cause the collection of a deposited coin in the coin box at the substation, or the actuation of the register therat to register the call, or the operation of the central office message register 20 to register therat the call.

(g) A key 707 herein termed "disconnect without register" or "collect," which will 25 when actuated from normal cause disconnection of the line of a calling substation and the line of a called substation from connection with the associated connecting circuit, and further will cause the restoration 30 to normal of the various switching devices employed in the connection. This key will not affect a deposited coin at a substation, the message register therat or the central office message registers.

(h) A key 708 herein termed "listening key." This key is "locking" and when actuated from normal connects the operator's telephone set with the associated connecting circuit, enabling the operator to converse 40 with the substations which may then be in connection therewith; also prevents selection of any of the connecting circuits of the same secondary group by any connecting circuit selector or secondary connecting 45 circuit selector having access to such circuits. The operator's telephone is automatically connected to the connecting circuits of the position upon their selection by a connecting circuit selector or secondary connecting circuit selector, and remains so 50 connected until immediately after operation of the recording keys associated with the position, when the operator's telephone is automatically disconnected from such connecting circuit. The arrangement of the 55 listening keys 708 are such, however, that after the automatic connection of the operator's telephone with a connecting circuit, should the listening key of any other 60 connecting circuit of the position be actuated from normal, the operator's telephone will be automatically disconnected from connection with the connecting circuit with 65 which it had been automatically connected and placed in connection with the connect-

ing circuit of the associated actuated listening key. Upon restoration to normal of an actuated listening key, the operator's telephone will be automatically restored to connection with the connecting circuit with 70 which it has been automatically connected, unless the recording keys of the position should have, in the meantime, been operated or unless disconnection of the line of the calling substation be in the meantime effected. 75

(i) A key 709 termed "rering" key. This key when actuated from normal causes the establishment of circuits, as will be herein-after described, which will cause connection of signaling current with the line of a called substation at the time connected with the associated connecting circuit, to actuate the signal or signals of such called substation. Should this key be actuated 80 from normal after the called substation has responded and "hung up," the called supervisory lamp 704 will be extinguished and the signaling lamp 703 will be brought into connection with the associated connecting 85 circuit and caused to burn steadily until the called substation responds or until disconnection of the line of the called substation from the connecting circuit is effected.

(j) A class of service register adapted at 95 the time of selection of the associated connecting circuit by a connecting circuit selector or a secondary connecting circuit selector, to be actuated, to register the class of the line of the calling substation then 100 extended to connection with the associated connecting circuit. This device is similar in construction to the allotter of Fig. 4, being of a well-known rotary switch construction adapted to move its brushes W^{18} forwardly, 105 only, and is provided with as many passive or bank contacts 710 as there are classes of lines, as calling lines, adapted to be connected with the associated connecting circuit. The cooperating brushes W^{18} are, as 110 explained in the case of allotter (Fig. 4), insulatingly mounted upon a shaft adapted to be positioned by a step-by-step movement effected by a well-known ratchet and pawl arrangement controlled by the motor magnet MM' . This register is also provided with contacts 711, 712 and 713 adapted to be closed at all positions, except normal, of the brushes W^{18} . The operation of this device is such that upon the extension of the 115 line of a calling substation to connection with the associated connecting circuit, the brushes W^{18} are caused to be rotated, by its motor magnet MM' in response to impulses from an interrupter I^2 , step by step to connection with a contact 710 corresponding to the class of the line of the calling substation, to, in the manner to be herein-after described, indicate to the operator the class 120 of the line of the calling substation connect- 125

ed with the associated connecting circuit. Upon disconnection, the brushes W^{19} are caused, in response to automatic actuations of its motor magnet MM' , to continue in the forward direction their step-by-step rotation to normal, out of connection with any of the passive contacts 710.

(b) A district selector (Fig. 10) provided with a plurality of rows or groups of passive contacts to which are multiply connected the selective terminals of the district trunks leading to and terminating in office selector switches (Fig. 14) and to local incoming selectors (Fig. 11). The trunks 10 terminating in the office selector switches in the present arrangement are divided into ten groups; those of each of the first four groups which are multiply connected to the passive contacts of a particular district 15 selector each comprising fifteen and are each connected to a separate set of passive contacts 1001, 1002, 1003 of a row of fifteen sets. Those of the remaining six groups terminating in a particular district selector are 20 each divided into two minor groups of fifteen each and are each connected to a separate set of passive contacts 1001, 1002, 1003 of two adjacent rows or minor groups. The trunks leading to and terminating in the 25 local incoming selector switches which terminate in a particular district selector are divided into three minor groups each comprising fifteen and are each connected to a separate set of passive contacts 1001, 1002, 30 1003 of three adjacent rows.

Coöperating with and adapted to engage any of the contacts 1001, 1002, 1003 are brushes W^{19} , W^{20} , W^{21} respectively. Associated with and common to the first row 40 of passive contacts of each group connected with trunks leading to office selectors comprising two rows is a group test relay GBC^4 (Fig. 14), and associated with and common to each of the first two rows of passive contacts connected with trunks leading to and terminating in the local incoming selectors is a group test relay GBC^2 (Fig. 11).

For each row of contacts 1001, 1002, 1003 there is provided a group contact 1004 which, 50 for each row with which is associated a relay GBC^2 or GBC^4 , is multiply connected with the normal contact of such relay. Also for each row or minor group of passive contacts, terminals of a minor group of trunk lines with which is associated a relay GBC^2 or a relay GBC^4 , there is provided a passive contact 1005, and for each minor group of contacts, terminals of trunk lines leading to office selectors, there is provided a contact 55 1006 in permanent connection with ground.

The brushes W^{19} , W^{20} , W^{21} are adapted to coöperate with the contacts 1001, 1002, 1003 respectively and the brushes W^{22} , W^{23} , W^{24} to coöperate with the group contacts 1004, 60 1005, 1006. The arrangement is such that

the brushes W^{19} to W^{24} inclusive are adapted to be rotated step by step in their primary selecting operation in response to impulses of current transmitted from the district section of the associated impulse transmitters 70 through the winding of the motor magnet PM^3 , until the brushes W^{22} , W^{23} , W^{24} engage the contacts 1004, 1005, 1006 corresponding to the first row or minor group of passive contacts, terminals of trunk lines of the desired district group, each leading to and terminating, as stated, in an office selector switch,—or—if the line of the called substation terminates in the same office as the line of the calling substation—until the 80 brushes W^{22} , W^{23} , W^{24} engage the contacts 1004, 1005 corresponding to the first row or minor group of contacts, multiply connected terminals of trunk lines, leading to and terminating in local incoming selector 85 switches.

If a desired group comprises more than one minor group, the brushes W^{19} to W^{24} inclusive are then automatically rotated in their primary selecting direction step by 90 step, responsive to automatic energizations of the motor magnet PM^3 , until a row or minor group of the selected group, containing a trunk line leading to an office selector or local incoming selector then idle, is engaged, or until the brush W^{22} engages a contact 1004 corresponding to the last minor group of the selected group, when the brushes W^{19} , W^{20} , W^{21} are automatically rotated step by step in their secondary selecting direction responsive to the automatic energizations of the motor magnet SM^3 , under the control of the relay ST^3 , into and out of engagement with the sets of passive contacts 1001, 1002, 1003 of the row until 105 the brushes engage a set multiply connected with an idle office selector or local incoming selector, as the case may be, when they come to rest and extend the connecting circuit to a connection with such office selector or 110 local incoming selector.

The normal contacts of PON^3 are, when the brushes in their primary selecting operation leave normal position, moved to their alternate position, and are not restored until the return of the brushes in their restoring operation to the position above normal. The contacts of SON^3 assume, when the brushes W^{19} , W^{20} , W^{21} start on their secondary selecting operation, their alternate position and are not restored until the return of the brushes to normal. The contacts of SOR^3 are closed when the brushes assume the position one step beyond the last set of passive contacts 1001, 1002, 1003 120 of any row or minor group, and are interrupted upon the return of the brushes during their restoration to the position coincident with the last set of contacts of the rows.

The interrupter I^4 , common to and as 125

sociated with the district selectors, is adapted, when the contacts of SOR³ are closed to transmit impulses of current through the winding of the relay 746 of the associated connecting circuit, to cause the flashing of lamp 704 to visually indicate to the operator that all of the trunk circuits of the selected group are at the time unselectable.

Each of the connecting circuits, in addition to the instrumentalities described, are provided with a plurality of relays which function as will be hereinafter described in connection with the operation of the system of the invention.

Each of the minor groups of connecting circuits is provided with a relay 714 which, during the simultaneous busy condition of each of the connecting circuits of the associated minor group, is energized, its contact closed and ground connected through common conductor 716 to the group test contacts 501 of the connecting circuit selectors (Fig. 5), and group test contacts 601 of the secondary connecting circuit selectors (Fig. 6), and thereby, as will be explained hereinafter, prevents selection by the connecting circuit selectors and secondary connecting circuit selectors of any of the connecting circuits of the associated minor group.

In order that the connecting circuits of each secondary group may be selected by connecting circuit finders, and the impulse transmitters associated therewith quickly placed in connection with the desired one of such connecting circuits, they may be divided into a desirable number of herein termed "connecting circuit finder groups," and for the purpose of illustration they are herein divided into three groups of ten each. For each such finder group a relay GBC' is provided, adapted, upon selection of any connecting circuit of the associated finder group, to be energized and control the starting of the allotted one of the connecting circuit finders to select, first, the corresponding connecting circuit finder group, and thereupon to select the desired one of the connecting circuits and thereby connect the associated impulse transmitter with such connecting circuit; connect ground through the common conductors 716 and 731 to the group test passive contacts 501 and 601 of the connecting circuit selectors and secondary connecting circuit selectors, to render the connecting circuits of the secondary group unselectable by any of the connecting circuit selectors or secondary connecting circuit selectors.

Common to each secondary group of connecting circuits appearing before an operator there are provided the following keys, which are effective only when the operator's telephone is connected with a connecting circuit. They are not effective when the keys 708 of two or more connecting circuits of the

same secondary group are simultaneously in their off-normal operated position:

(a) "Line flash" key 720, adapted when actuated from normal to cause the line lamp or lamps LL, LL², LL³, (Fig. 1, Fig. 2, Fig. 3), of the line of a calling substation connected to the connecting circuit, the listening key 708, of which is then operated from normal, to flash and indicate to the operator the number or numbers of the line of the connected calling substation.

(b) Key 721 herein termed "disconnect key," which will, when actuated from normal, cause the disconnection of the line of the called substation from the effective connecting circuit without affecting (if so equipped) the coin box apparatus, substation message register or the central office message register of the line of the calling substation then in connection with the same connecting circuit.

(c) Key 723 herein designated "coin collect key," which will, when actuated from normal, if the calling substation at the time connected to the effective connecting circuit be equipped with a coin box or substation message register, cause collection of a deposited coin or the operation of the substation message register.

(d) Key 722 entitled "coin return key," which will, when actuated from normal, if the calling substation connected with the effective connecting circuit be equipped with a coin box, cause return of a deposited coin to the party calling.

(e) Key 724 herein termed "disconnect key," which will, when actuated from normal, cause disconnection from the effective connecting circuit of the line of a called substation, and if the substation of such called line has answered and "hung up" will cause (if so equipped) either the collection of a deposited coin, the operation of the message register at the substation, or the operation of the office message register of the line of the calling substation connected therewith.

(f) A set of ring-back keys 725, 726, 727, 728, arranged when actuated from normal to connect signaling current to the line of a calling substation then in connection with the effective connecting circuit to selectively signal calling substations. Associated with the keys 725 to 728 inclusive and adapted to be actuated from normal in response to the actuation of any one of them, is a set of master contacts 729, which function as will be hereinafter described.

There is also provided common to the connecting circuits of each secondary group:

(a) A relay 730, adapted, when all of the connecting circuit finders of Fig. 8 associated with a secondary group of connecting circuits are in an off-normal position, to be energized, its contacts closed and ground

connected through conductors 716 and 731 to the corresponding test contacts 501 of the connecting circuit selectors and to the corresponding test contacts 601 of the secondary connecting circuit selectors, and render any of the connecting circuits of the associated secondary group unselectable.

(b) Relay 732, which is differentially wound and adapted, whenever the listening keys 708 of two or more associated connecting circuits are simultaneously in their off-normal actuated position, to be energized to interrupt its normal contacts and to close its alternate contacts and render, in the manner to be hereinafter described, ineffective the operation of any of the keys 721 to 728 inclusive.

(c) Relay 733, which is energized during the actuation of the listening key 708 of any of the associated connecting circuits to connect ground through its alternate contacts and conductors 716, 731 to the corresponding passive contacts 501 and 601, to prevent selection, by the connecting circuit selectors 25 and secondary connecting circuit selectors, of any of the connecting circuits of the associated secondary group.

(d) A set of lamps 734, which when illuminated visually indicate to the operator the class of the line of a calling substation then in connection with the connecting circuit at the time connected to the operator's telephone.

(e) Relay 735 associated with interrupter I⁸ adapted, in response to actuation of key 709, to control connection of signaling current to the line of a called substation terminating in a distant office.

(f) Relay 736, adapted when energized to cause the illumination of lamp 737 to visually indicate to the operator the actuation of a substation coin box or substation message register then in connection with the effective connecting circuit.

(g) A position message register comprising relays 741, 742, 743, 744 and recording magnet 765, adapted when actuated to record the connection of a calling line, equipped with a central office message register, with a called line and cause the illumination of an associated lamp 745 to indicate to the operator the actuation of the central office line message register of the line of the calling substation then connected with the effective connecting circuit.

(h) A plurality of connecting circuit finders (Fig. 8) with each of which is associated an impulse transmitter (Fig. 9, Parts 1 and 2), each adapted, when idle, to be, upon the automatic extension of the line of a calling substation to connection with any of the connecting circuits of the associated secondary group, sequentially automatically started to rotate its brushes responsive to actuations of its motor magnet PM¹⁴ until

brush W¹⁹ engages a group test contact 801 multiply connected to the normal contact 740 of the relay GBC' of the connecting circuit finder group in which is included a connecting circuit connected with the line of a calling substation awaiting extension to connection with the line of a desired substation, and to thereafter automatically rotate its brushes W²⁰, W²¹, W²², W²³ step by step responsive to actuations of its motor magnet SM¹⁴ into and out of connection with their associated sets of passive contacts 802, 803, 804, 805, multiple terminals of the connecting circuits of the selected connecting circuit finder group, until the desired set is engaged, when the brushes W²⁰, W²¹, W²², W²³ are brought to rest in connection therewith and the associated impulse transmitter extended to connection with such selected connecting circuit.

(i) An allotter (Fig. 8), which is similar in construction to the allotter of Fig. 4, adapted to move its brushes W²⁴, W²⁵, W²⁶, W²⁷, forwardly only, into and out of connection with their associated passive contacts 806, 807, 808, 809, in response to automatic energizations of its motor magnet MM², which magnet is in turn controlled by the associated test relay T'. This allotter controls the sequential connection of the connecting circuit finders and their associated impulse transmitters with the connecting circuits of their associated secondary group.

(j) A set of "office" recording keys (Fig. 9, Part 1), one key for each office of the system of which only eleven are shown, each adapted, when actuated from normal, to cause the district and office sections of an allotted one of the associated impulse transmitters to assume positions corresponding to the district and office in which terminate the lines of substations, as called substations.

(k) A set of numerical recording keys (Fig. 9, Parts 1 and 2), divided into four groups of ten each, designated "thousands," "hundreds," "tens" and "units" respectively, adapted when a key in each group is actuated from normal to cause the associated sections of the allotted impulse transmitter to assume positions corresponding to the various digits of the numerical designation of a called substation.

The recording keys may be of any desired construction and each is adapted when actuated from normal to be locked in such position until the brush W²⁹ of each section of the associated operatively connected impulse transmitter is brought to rest in connection with its passive contacts 911, multiple terminals of the recording keys actuated, when the release magnets 906 of the respective group are energized and automatically restore the off-normal actuated ones of the keys.

(l) A plurality of impulse transmitters

(Fig. 9, Parts 1 and 2), each associated with a connecting circuit finder (Fig. 8), and each divided into sections designated "district," "office," "thousands," "hundreds," 5 "tens," "units." Each section comprises a brush $W^{29'}$ adapted, when a recording key of the associated group is actuated from normal, to be automatically rotated step by step, responsive to energizations of its motor 10 magnet MM^3 , into and out of engagement with its associated row of passive contacts 911, multiple terminals of the keys of the associated group, until the brush engages the passive contact of the actuated key, 15 when the brush comes to rest in engagement therewith. The brushes of each of the sections are simultaneously started on their selecting operation, and when each has engaged its contact 911, the multiple terminal 20 of an actuated key, a circuit is established which energizes the associated relay 924 which interrupts circuit through the magnet MM^3 , and, in the manner hereinafter to be described, establishes a circuit which causes 25 the energization of the restoring magnets 906 of each group of recording keys, resulting in the restoration of the actuated ones thereof. Following immediately thereafter a circuit is established for the relay T' of 30 the allotter (Fig. 8), which closes a vibratory circuit for the motor magnet MM^2 , and responsive thereto the brushes $W^{24'}$ to $W^{27'}$ inclusive, of the allotter are rotated out of connection with their then engaged set of 35 passive contacts and into engagement with the set of passive contacts, terminals of a connecting circuit finder in normal position and with which is associated an impulse transmitter also in normal position, thereby 40 placing the recording keys, a connecting circuit finder and its associated impulse transmitter in condition to be utilized in extending the line of the calling substation next selecting any one of the connecting circuits 45 of the associated secondary group, to connection with a desired called substation.

Following the release of the recording keys and the closure of the circuit for causing the disconnection of the brushes of the 50 allotter from the passive contacts of a connecting circuit finder and associated impulse transmitter, the brushes $W^{29'}$ of each section of an actuated impulse transmitter are caused to be sequentially rotated back 55 from their adjusted positions in connection with the multiple terminals of actuated keys to their normal positions, each transmitting, during their return to normal, impulses of current to the directly actuated 60 ones of the selector switches to cause selection of, and connection of the desired called substation corresponding to the recording keys actuated.

Each section of each transmitter, for the 65 sake of uniformity, may be provided with

twenty-six passive contacts 911, herein termed "positions." In addition, each section is provided with a contact 912 adapted to be closed at all positions from 2 to 26 inclusive, a contact 913 closed at normal or 70 first position only, a contact 914 closed at positions 5 to 26 inclusive, a contact 915 disconnected at all positions but connected for all sections, except the units section, between each position from 5-1/2 to 24-1/2 inclusive, and for the units section from 7-1/2 to 16-1/2 inclusive, a contact 916 closed at normal position only, a contact 917 closed at all positions except normal. Each section, except the units section, is, in addition, 75 provided with a contact 918 which is closed at the first or normal position only. The tens section is provided with a contact 919 which is closed at positions 2 to 3 inclusive, and a contact 920 closed at positions 13 to 80 26 inclusive. The units section is provided with a contact 921 closed at positions 2 to 4 inclusive, a contact 922 closed at positions from 2 to 6 inclusive, and a contact 973 adapted to be closed at positions from 6 to 85 18 inclusive.

Mechanical arrangement of impulse transmitters.

Referring now to the mechanical structural arrangement of the sections of the impulse transmitters illustrated in Fig. 9, Parts 1 and 2, and in Fig. 21, Parts 1 and 2, by which the directive selective operations of the selector switches are controlled, each 95 section may be similar and may take various forms, but are preferably constructed along the lines indicated in Figs. 22 to 33 inclusive, in which it will be observed that the passive contacts 911 are mounted between arcuate 100 plates 924 suitably carried on a base 925 and arranged so as to present their contacting ends for engagement with the coöperating brushes $W^{29'}$. These contacts are suitably insulated from each other and have 105 their outer ends arranged for the attachment of suitable conductors, the multiple terminals of the recording keys.

The shaft 926 is journaled in the base 925, and carries rigidly fastened thereto the 110 ratchets 927, 928, 929, the adjustable stop 930, retractile spring casing 931, a plurality of circuit changing switch contact controlling cam disks 932, and the brushes $W^{29'}$. The gear 934 meshes with pinion 935 and carries a pawl 936 which coöperates with the ratchet wheel 929. The escapement ratchet wheel 937, rigidly fastened to the pinion 935 and loosely mounted on the base 925, coöperates with the pallet 938 to regulate the 115 speed of the return to normal of the brushes $W^{29'}$. Also loosely engaging the base 925 is the angular piece 939, to which is secured a collar 940 loosely surrounding the shaft 926, to which is secured the inner end of the re- 120 125 130

tractile spring 941, the outer end of said spring being secured to its casing 931 which, as stated, is adjustably rigidly secured to the shaft 926.

- 5 The brushes W^{29} are adapted to be moved from their normal positions to their various selecting positions by the mechanism of the motor magnet MM^3 , and to be returned to their normal positions by the spiral retractile spring 941. The motor magnet MM^3 is suitably mounted on the base 925, and its armature 942 is provided with a suitable driving pawl 943, which is adapted to engage the teeth of ratchet wheel 927 to cause 10 the rotation of the shaft 926. The pawl 943 is spring-pressed toward the ratchet wheel, but when in its retracted position is withdrawn from engagement therewith by the stop 944 riding upon an adjacent surface of 15 the pawl. The forward stroke is limited by any suitable means, as for instance, by the pawl engaging a portion of the bracket 945.

The motor magnet MM^3 is provided with an interrupter of a well-known type so arranged that immediately following the closure of the initial energizing circuit, such circuit will be maintained closed until the completion of the forward stroke of the armature 942, at which time circuit through 20 the winding of the magnet is interrupted and so remains until the return to normal position of the armature, regardless of any change of condition in the external circuits or apparatus. The arrangement of this interrupter is such that spring 946 is connected immediately after the starting of the forward stroke of the armature with the spring 947 which, as will be hereinafter described, operates to establish a local circuit for the 25 magnet. Cam 948 by its coöperation with the oscillating lever 949 causes the lever spring 950 to break and make connection with its associated contact spring 951 in the manner shown in Fig. 25. The angular movement of the lever 949 is limited by upturned projections of the piece 952.

For controlling the restoration of the shaft 926, after its actuation from normal, each section is provided with a magnet RM^3 secured in any suitable manner to the base 925. The magnet RM^3 is provided with an armature 953, to which is attached an angular piece 954 through which extends the adjusting screw 955, which acts to limit the 50 back stroke of the armature. The magnet carries spring 956 which coöperates with associated contact springs 957, 958. The spring 956 also acts to restore the armature 953 to its normal position upon the interruption of 55 flow of current through the winding of the magnet. The armature 953 projects outwardly from the magnet and is arranged to engage the rearward extension of the retaining pawl 959 in a manner such that when the 60 armature is attracted, responsive to the ener-

gization of the magnet, pawl 959 is rocked about its pivot and caused thereby to be disengaged from the ratchet 928.

Following the energization of the magnet RM^3 and the disconnection thereby of the pawl 959 from connection with the ratchet wheel 928, the shaft 926 and all parts connected thereto are, under tension of the retractile spring 941, retrograded to their normal position at a uniform rate as controlled 75 by the escapement ratchet wheel 937 and pallet 938.

During the return to normal of the shaft 926, by means of the disks 932, impulses of current, varying in number according to the position at which the brushes were set, which in turn depends upon the recording key actuated, are transmitted through contact 915 (see Fig. 9) to cause the actuation of the selector switches, as will hereinafter be described.

The arrangement of each section of the transmitters is such that after the initial energization of the magnet RM^3 , a holding circuit is established which maintains the magnet in an energized position until the shaft 926 and the parts connected thereto reach their normal position, when the magnet RM^3 is automatically deenergized and its armature returned to normal.

As stated, the speed at which the shaft 926 returns to normal is controlled by the escapement ratchet wheel 937 and its coöperating pallet 938. This is brought about through the coöperation of gear 934 with pinion 935 in that at the beginning of the retrograde motion of the shaft 926, the pawl 936 engages a tooth in the ratchet wheel 928, and as the pawl 936 is fastened to the gear 934, the gear is rotated with the ratchet wheel 928, and as gear 934 meshes with the pinion 935, to which is fastened the escapement ratchet wheel 937, the pinion 935 and ratchet wheel 937 are rotated, causing pallet 938 to vibrate and in the well-known manner prevent acceleration of the speed of rotation of the shaft 926.

The drawing illustrates in Figs. 27 to 33 inclusive, seven cam disks 932, each having associated therewith contact springs arranged in a particular order and which correspond to the units section, diagrammatically illustrated in Fig. 9, Part 2. The particular combination of these disks vary in number and arrangement in the different 115 sections of the transmitters. As such variations as are employed may obviously be accomplished, they are not herein illustrated.

Arrangement of local incoming selectors.

Referring now to the local incoming selectors (Fig. 11) which are similar to the district selectors of Fig. 10, the passive contacts 1101, 1102, 1103 are divided into ten 130

- groups, each comprising two rows or minor groups of fifteen sets each, to which are multiply connected the selective terminals of hundreds selector switches (Fig. 12).
- 5 Associated with the first minor group of each group of trunks, multiply connected with the passive contacts of a local incoming selector, is a relay GBC³ (Fig. 12) adapted, when all the trunks of the associated
- 10 minor group are busy, to be energized and prevent selection by a local incoming selector, an interoffice incoming selector (Fig. 15) or a manual incoming trunk selector (Fig. 19, Part 2) of the associated minor group.

For each minor group of trunk lines, each terminating on a set of passive contacts 1101, 1102 and 1103 of a row, there is provided a set of group contacts 1104, 1105 and 1106, with which coöperate brushes W²⁵, W²⁶ and W²⁷, respectively. The contacts 1104, corresponding to the first minor group of each group, are connected to the normal contact of the corresponding relay GBC³ (Fig. 12) and the contact 1104, corresponding to the second and last minor group of each group, are in permanent connection with ground. The contact 1105 corresponding to the first minor group of each group of trunk lines, multiply connected with contacts 1101 to 1103, inclusive, is connected with the alternate contact of the relay GBC³ corresponding to the group. The passive contacts 1106 of each group are connected with a source of signaling current adapted to be connected, through winding of relay GTR, with the lines of called substations of the corresponding thousands group to selectively actuate the signal device or devices of such substations.

40 The contacts PON⁴, SON⁴ and SOR⁴ are actuated as stated in connection with the district selector (Fig. 10). The interrupter I⁴ is also associated with the local incoming selectors, and adapted upon closure of the contacts of SOR⁴ to transmit impulses of current to cause the flashing of lamps 704 of the connecting circuits, as stated in reference to the district selectors.

50 The operation of the local incoming selectors is such that the brushes W²⁵ to W³⁰ inclusive, are rotated step by step in their primary selecting operation in response to impulses transmitted from the thousands section of the impulse transmitters (Fig. 9, Part 1) through the winding of the motor magnet PM⁴, until the brushes W²⁸, W²⁹, W³⁰ engage contacts 1104, 1105, 1106 respectively corresponding to the first row or minor group of contacts 1101, 1102, 1103, multiple selective terminals of a desired group of trunk lines leading to and terminating in hundreds selector switches. If all of the trunk lines of the minor group, to which

65 impulses from the thousands section of the impulse transmitters, be at the moment simultaneously busy, then the brushes will be automatically rotated to the next or last minor group of such group, and the brushes 70 W²⁵, W²⁶, W²⁷ thereupon automatically rotated step by step in their secondary selecting operation responsive to energizations of the motor magnet SM⁴, under the control of the relay ST⁴, into and out of engagement 75 with the sets of passive contacts 1101 to 1103 inclusive, until a set, multiple terminals of an idle hundreds selector, is engaged, when they come to rest and extend the connecting circuit to connection with such selected hundreds selector.

80 The characteristics of the relays GTR are such that they will not, when in circuit with the signaling apparatus of a connected substation, be energized to an extent sufficient 85 to cause the interruption of their contact. But upon response at the called station and the removal thereby of the signaling apparatus from circuit, and the connection of the talking apparatus of the substation with the 90 line, sufficient current from the signaling source will flow through the winding of said relays to cause their actuation to a sufficient extent to interrupt their contact, which acts to cause disconnection of the source of signaling current from the connected line and the establishment of the talking connection in the manner to be hereinafter described in connection with the operation of the system.

85 Associated with each local incoming selector is a differentially wound relay 1108 and a relay 1109 adapted to control the connection of signaling current through brush W³⁰ and winding of relay GTR with the lines of the called substations in the manner 105 to be hereinafter described.

Arrangement of hundreds and final selectors.

90 The hundreds selectors (Fig. 12) are each 110 provided with five groups of thirty sets of passive contacts 1201, 1202 and 1203, with which coöperate the brushes W³¹, W³² and W³³ respectively. To each set of passive contacts of each group are multiply connected selective terminals of trunk lines leading to and terminating in the corresponding group of final selectors (Fig. 13). In the illustrated arrangement each group 115 of passive contacts 1201 to 1203 is divided 120 into two minor groups or rows of fifteen sets each. Common to and associated with the trunk lines connected with the first minor group of each group is a relay GBC⁶, which, when all of the trunks of the associated 125 minor group are simultaneously busy, is energized to prevent selection by the hundreds selectors of the corresponding minor group, and for each minor group of contacts 1201 to 1203, inclusive, there is provided a group 130

passive contact 1204 and a group passive contact 1205 with which coöperate brushes W^{34} and W^{35} , respectively.

The contact 1204 of the first minor group 5 of each group is multiply connected with the corresponding contact of all hundreds selectors to the passive contacts of which are multiply connected selective terminals of the corresponding group of final selectors, 10 and leads to and terminates in the normal contact of the corresponding relay GBC⁶.

Contact 1204 of the second and last minor group of each group is permanently connected with ground. The contact 1205 corresponding 15 to the first minor group of each group is likewise multiply connected to the corresponding contact of each of the hundreds selectors, to the passive contacts of which are multiply connected the selective 20 terminals of the final selectors of the corresponding minor group, and leads to and terminates in the alternate contact of the corresponding relay GBC⁶, acting, when all of the trunk lines of the corresponding minor 25 group are simultaneously in use, to prevent selection of such minor group by the hundreds selectors.

The contacts of PON⁶, SON⁶ and SOR⁶ are actuated in the manner described in connection 30 with the district selector (Fig. 10). The common interrupter I⁴ is associated with the hundreds selectors and adapted when the contacts of SOR⁶ are closed to cause the flashing, in the manner stated, of 35 the lamp 704 of the connecting circuits. The operation of the hundreds selectors is such that the brushes W^{31} to W^{35} inclusive are rotated step by step in their primary selecting operation in response to impulses transmitted 40 from the hundreds section of the impulse transmitters (Fig. 9, Part 2 and Fig. 21, Part 1), through the winding of the motor magnet PM⁵ until the brushes W^{34} , W^{35} engage contacts 1204, 1205 respectively corresponding 45 to the first row or minor group of contacts 1201, 1203, terminals of trunk lines of the desired hundreds group each leading to and terminating in a final selector switch, to the passive contacts of which are multiply connected terminals of the line of a desired called substation. If all of the trunk 50 lines of such first minor group be simultaneously busy, then the corresponding relay GBC⁶ (Fig. 13) will be energized and the brushes W^{31} to W^{35} inclusive automatically rotated in their primary selecting operation beyond the first minor group in response to the energization of the motor magnet PM⁵ under the control of relay PT⁵ to the second 55 and last minor group, when the brushes W^{31} and W^{33} inclusive are automatically rotated step by step responsive to energizations of motor magnet SM⁵ under the control of relay ST⁵ into and out of engagement with 60 the sets of passive contacts 1201 to 1203 in- 65

clusive, until they engage a set, the multiple selective terminals of an idle final selector switch, when they come to rest and extend connection to such final selector.

The sets of passive contacts 1301, 1302, 70 1303, 1304, of the final selectors (Fig. 13) with which coöperate brushes W^{36} to W^{39} inclusive, are divided into twenty groups of ten sets each, to which are directly multiply connected the called terminals of the substation lines. Therefore, each final selector 75 may comprise the multiple called terminals of the lines of 200 substations.

If any of the substation lines of a hundreds group multiply connected with the 80 passive contacts of a group of final selectors comprise lines leading to a private branch exchange or other similar class, and if such lines exceed ten in number, then they, in the illustrated arrangement, are divided into 85 minor groups of ten lines each, and for each such minor group, except the last, a relay GBC⁷ (Fig. 2) is provided, adapted, when all the lines of the associated minor group are simultaneously busy, either as calling or 90 called lines, to be energized to prevent the selection of the minor group and the extension of the line of a calling substation to connection with a line thereof.

For each such minor group, except the 95 last, there is provided a group passive contact 1306 (with which coöperates brush W^{41}), multiply connected with the corresponding contact of each final selector of the group and the alternate contact of the corresponding relay GBC⁷. 100

For each row of passive contacts 1301 to 1304, inclusive, there is provided a group contact 1305, with which coöperates brush W^{40} . The contacts 1305, corresponding to each 105 minor group, except the last minor group of contacts connected with lines leading to a substation of the private branch exchange class, which comprise two or more minor groups, is multiply connected with the corresponding contact of each final selector, and to the normal contact of the corresponding relay GBC⁷. The contacts 1305 of each of the other minor groups of each of the final selectors are permanently connected 110 with ground.

The contacts of PON⁶ and SON⁶ are actuated as described in connection with the district selector. The final switches each comprise, in addition, a line test relay LTR so adjusted as not to be actuated when the brush W^{38} is brought to rest in connection with the contact 1302 of a line then in connection with the brush W^{38} of some other final selector, or in connection with brush W^3 of a line finder 120 (Fig. 4), but will be actuated to open its normal contact and to close its alternate contacts when the brush W^{38} is brought to rest in engagement with any one of its associated contacts 1302, terminals of lines 125 130.

then idle, a polarized relay XT, relay 1307, connecting relay CR^e, relay BFR, and slow release relays 1308 and 1309.

Common to and associated with the final 5 selectors is the interrupter I⁵, adapted, upon the energization of relays BFR, responsive to attempted connection with the terminals of busy lines to transmit impulses to the connecting circuits to cause the flashing in 10 a characteristic manner of the lamps 704 to visually indicate to the operators the busy condition of the line or lines of the called substations.

The arrangement is such that the brushes 15 W³² to W⁴⁰, inclusive, are rotated step by step in their primary selecting operation in response to impulses of current transmitted from the tens section of the impulse transmitters through the winding of magnet PM^e 20 until the brushes are brought to the position opposite the row containing the multiple terminals 1301 to 1304, inclusive, of the line or lines of the desired called substation, whereupon, if the substation be of the private branch exchange class and the lines leading thereto exceed ten, the brushes will be automatically rotated, responsive to automatic energizations of the magnet PM^e, until the row containing an idle line or until 25 the last row is reached, when the relay ST^e will be energized and the brushes W³² to W³⁹ inclusive rotated into engagement with the first set of contacts of the row. Thereafter the brushes are automatically rotated step by step into and out of connection with the contacts of the row, responsive to the automatic energizations of the magnet SM^e to connection with the first engaged 30 set of contacts 1301 to 1304, inclusive, multiply connected with an idle line, when they are brought to rest in connection therewith; or, if all such lines of the selected group be 35 busy, until the brushes reach the position one step beyond the last set of contacts of the selected row, whereupon the relay BFR will be energized and interrupter I⁵ connected, to cause the flashing of lamp 704 of the connected connecting circuit.

If the substation be of the private branch 40 exchange class and the lines leading thereto do not exceed ten in number, following the selection of a row, responsive to the impulses transmitted from the tens section of the impulse transmitter, the relay ST^e will be energized and thereafter the brushes W³² to W³⁹, inclusive, rotated step by step, responsive to the impulses transmitted from the units section of the impulse transmitter, through the winding of motor magnet SM^e 45 to connection with the passive contacts multiply connected with the first line leading to the substation, whereupon they are brought to rest in engagement therewith unless such line be, at the time, busy, in 50 which event the brushes will be rotated, step

by step, into and out of engagement with the contacts multiply connected with the busy lines until the terminals of an idle line are engaged, when they will be brought to rest in engagement therewith, or until 70 they have passed one step beyond the last set of contacts connected with a line leading to the desired substation, into engagement with the next succeeding set of contacts, terminals of a line of some class other 75 than the private branch exchange class, or until the brushes reach the position one step beyond the last set of contacts of the row, when the relay BFR will be energized and the interrupter I⁵ connected to cause the 80 flashing of lamp 704 of the connecting circuit.

If the line be of any other class than the private branch exchange class, then, following the selection of a row of contacts, responsive to the impulses transmitted from the tens section of the impulse transmitter, the relay ST^e will be energized and thereafter the brushes will be rotated into and out of connection with the contacts of the 85 row, responsive to the impulses transmitted from the units section of the impulse transmitter, through the winding of the motor-magnet SM^e, to connection with the contacts 90 1301 to 1304, inclusive, multiple terminals 95 of the line of the desired substation; following which, if the line be busy, the relay BFR will be energized and the interrupter I⁵ connected, to cause the flashing of the lamp 704 of the connecting circuit, or, if the 100 line be idle, the relay LTR will be energized, following which the conversational circuit connection will be established in the manner to be hereinafter described in connection with the operation of the system. 105

Arrangement of office selectors.

The passive contacts 1401, 1402, 1403, of the office selectors (Fig. 14) with which brushes W⁴², W⁴³, W⁴⁴ cooperate, are divided 110 into as many groups as there are offices allotted to the district, which in the herein illustrated embodiment of the invention may comprise ten such groups, each comprising two minor groups of fifteen sets 115 each, to each of which are multiply connected the selective terminals of trunk lines, those of each group leading to a different central office and there terminating, if the office be equipped as an automatic call distributing office, in an interoffice incoming selector (Fig. 15), or if the office be a 120 manual office, they terminate in a manually actuated plug switch (Fig. 16) which is adapted to be connected with the multiple 125 jacks of the lines terminating in such office as indicated in Fig. 16.

Individual and common to the first minor group of each of the groups of trunks multiply connected to the passive contacts 1401, 130

1402, 1403 leading to interoffice incoming 5
selectors, is a relay GBC^s (Fig. 15, Part 1), and common to the first minor group of each group of trunks which lead to the manual offices and there terminate in the mentioned 10
plug switch terminal, is a relay GBC^s (Fig. 16, Part 1). Each relay GBC^s and GBC^s is adapted, when all of the trunk lines of its associated minor group are simultaneously in use, to be energized to prevent the 15
selection of the corresponding minor group by the office selectors.

Common to each row or minor group of contacts 1401 to 1403 inclusive is a group 15
contact 1404 with which coöperates brush W⁴⁵. With the contact 1404 of the first minor group of each group there is multiply connected a conductor leading to and terminating in the normal contact of the relay 20
GBC^s or the relay GBC^s, depending upon whether the trunks of the group lead to an automatic call distributing office or to a manual office. The contact 1404 of the second minor group of each group is directly connected to ground. 25

Common to the first minor group of each group of contacts 1401 to 1403 inclusive is a group contact 1405, with which coöperates brush W⁴⁶, to which is multiply connected a conductor leading to and terminating in the alternate contact of the corresponding relay GBC^s or GBC^s. 30

The arrangement is such that the brushes W⁴² to W⁴⁶ inclusive are rotated in their primary selecting operation in response to impulses of current transmitted from the office section of the impulse transmitters through the winding of magnet PM^s until the brushes W⁴⁵ and W⁴⁶ engage the contacts 1404 and 1405 respectively corresponding to the first row or minor group of contacts 1401 to 1403 inclusive, with which are connected multiple terminals of the trunk lines of the group leading to the desired office. Thereupon, if all of the trunk lines connected to the passive contacts of such minor group be busy, the magnet PM^s will be automatically energized, under the control of relay PT^s, and the brushes W⁴³ to 45
W⁴⁶ inclusive moved to the second minor group of the selected group, when the brush W⁴³ will come to rest in engagement with the corresponding contact 1404 and the brushes W⁴² to W⁴⁴ inclusive will be automatically rotated step by step in their secondary selecting operation, responsive to automatic energizations of the secondary magnet SM^s, under the control of relay ST^s, into and out of engagement with the sets 50
of passive contacts 1401 to 1403, until a set, to which is multiply connected terminals of a trunk line then idle, and which leads to and terminates in either an interoffice incoming selector (Fig. 15) or in a manually actuated plug switch (Fig. 16), is engaged, when 55
60
65

they come to rest and extend the connecting circuit, then in connection with the office selector, to connection with such selected interoffice incoming selector or manually actuated plug switch terminal. 70

The contacts PON^s, SON^s and SOR^s are actuated as described in connection with the district selector. The common interrupter I^s is also associated with the office selectors and adapted, when their contacts SOR^s are closed to transmit impulses to the connecting circuit then in connection therewith to operate the associated lamp 704, to visually indicate to the operator that all available paths to the desired office are busy, and that the connection with the substation of the line desired cannot then be established. 75
80

Arrangement of interoffice incoming selectors.

The interoffice incoming selector (Fig. 15, Parts 1 and 2) is provided with twenty rows of sets of passive contacts 1502, 1503, 1504, with which coöperate brushes W⁴⁷, W⁴⁸, W⁴⁹ respectively, and which are divided into ten groups, each comprising two minor groups or rows of fifteen sets each. Multiply connected to each set of contacts 1502 to 1504 inclusive of each group are the selective terminals of a hundreds selector as described 95
in connection with the local incoming selector (Fig. 11). Also as described in connection with the local incoming selector (Fig. 11), for each minor group of passive contacts, terminals of trunk lines leading to hundreds selectors, there is a group contact 1505 with which coöperates a brush W⁵⁰, which for the first minor group of each group is multiply connected to a conductor leading to and terminating in the normal contact of the relay GBC^s (Fig. 12). Contact 1505 of the second minor group of each group is permanently connected with ground. 100
105

Common to and associated with the first minor group of each group of trunk lines multiply connected with the passive contacts 1502 to 1504 inclusive, is a contact 1506 with which coöperates brush W⁵¹ and to which is multiply connected a conductor leading to and terminating in the alternate contact of the corresponding relay GBC^s. Common to each minor group of contacts 1502 to 1504 inclusive is a contact 1507 with which coöperates brush W⁵² and to which is connected a source of signaling current adapted to be, through brush W⁵² and the winding of relay GTR', connected, upon selection, with the lines of desired called substations to cause the actuation of the substation signals. As explained in connection with the relay GTR (Fig. 11), the relay GTR' will not be, when included in circuit with the substation signaling apparatus, actuated sufficiently to interrupt its contact, 110
115
120
125
130

but upon the response by a party at the called substation sufficient current will flow through winding of the relay GTR' to cause its actuation to interrupt its contact, to bring

5 about the disconnection of signaling current from the line of the called substation.

The relay 1508 is differentially wound and corresponds to the relay 1108 described in connection with the local incoming selector 10 (Fig. 11). Likewise, relay 1509 corresponds to relay 1109 (Fig. 11).

Associated with each trunk terminating in an interoffice incoming selector, and as shown in Fig. 15, Part 1, is a relay 1501, 15 which is located at the outgoing end, a repeating coil 1510, a relay 1511 provided with a winding of such resistance as to prevent, when connected in circuit, a sufficient flow of current to cause the actuation of the relay 746 of the connecting circuits, but which when its high winding is short circuited will allow sufficient current to flow over the trunk circuit to bring about the energization of relays 746; relays 1512, 1513, 1514 (responsive to impulses transmitted from the impulse transmitters, Fig. 9, Parts 1 and 2), a relay 1515, which is slow to release its armature after interruption of its energizing circuit, a relay 1516 also slow to release 20 its armature after interruption of its energizing circuit, a relay 1517 adapted to close its alternate contact before interrupting its normal contact, and relay 1520—all of which will be described hereinafter in connection 25 with the description of the operation of the invention.

The contacts PON^o, SON^o and SOR^o are actuated as hereinbefore described in connection with the district selector (Fig. 10).

40 The interrupter I⁴ of the office is common to and associated with the interoffice incoming selectors, adapted upon the closure of their contacts SOR^o to transmit impulses to the connecting circuits, to flash the associated lamps 704, to visually indicate to the operator that all trunk lines leading to and terminating in hundreds selectors of a selected group are busy and unselectable, and that the connection cannot then be established.

Arrangement of trunks from office selectors to manual office.

Referring now to the trunks terminating 55 on the passive contacts of the office selectors, which lead to and terminate in the manually actuated plug switch terminals at the manual offices, and utilized for establishing connections between lines of calling substations 60 terminating in automatic call distributing offices and lines of called substations terminating in manual offices. As stated, each of these trunks terminates in a manually actuated plug switch, which comprises con-

tacts 1602, 1603 and 1604, adapted to be connected to multiple jack contact terminals 1605, 1606, 1607 respectively of the lines of substations, as called substations.

Individual to and associated with each of these trunk lines, at the outgoing end, is a relay 1601, which is slow to release its armature, adapted to control the automatic selection of its terminals; a relay 1618 corresponding to the relay 1511 of Fig. 15; a repeating coil 1609; a supervisory relay 1610; 70 a GTR² relay, to the winding of which is connected a source of signaling current adapted to be connected with the lines of called substations to actuate the signaling mechanism thereat, having the characteristics of relays GTR (Fig. 11) and GTR' (Fig. 15); a differentially wound relay 1615 having the characteristics of relay 1108 (Fig. 11); relay 1508 (Fig. 15, Part 2); a relay 1616 which is slow to release its armature after interruption of current through its windings; a relay 1617 also slow to release its armature after interruption of current through its winding; relays 1619, 1620, 1621, 1622, 1623, 1624, 1625, 1626; and signal lamps 1627, 1628—the operation of which will each and all hereinafter be described in connection with the operation of the system of the invention; also a relay 1629 which is actuated following selection 95 of the trunk by an office selector responsive to impulses transmitted from the office section of the impulse transmitters (Fig. 9) to render, by the opening of its normal contact, the automatic selection of its associated trunk line possible by the associated cord finders (Fig. 17) as hereinafter described.

The trunk lines terminating in the manual plug switches which appear before an operator are, in respect to their automatic selection by the associated cord finders of Fig. 17, grouped as described in connection with the connecting circuits of Fig. 7, Parts 1 and 2; that is, assuming that the manual plug switch terminals of fifty trunk lines appear before an operator, then they may be divided into five groups; herein termed cord finder groups, each comprising ten such trunk lines, which are multiply connected to a row of passive contacts of the associated cord finders (Fig. 17) of the position. For each such group of ten trunk lines, there is provided a relay GBC¹⁰ which is energized responsive to the closure 105 of the alternate contact of the relay 1629 of any one of the trunks of the cord finder group. The relays GBC¹⁰ when energized will cause an allotted one of the cord finders 110 of Fig. 17 to be automatically started to 115 select first, the group containing multiple terminals of a trunk line which has been selected by an office selector, and to there-

after automatically select the set of passive contacts multiply connected with such trunk line.

The line circuits at the central offices of the manual substations may comprise any of the well-known arrangements, and as herein illustrated are provided with a line relay LR^4 , a line signal lamp LL^4 , a cutoff relay CO^4 and a plurality of multiple jacks, of which only one is shown, each comprising contacts 1605, 1606, 1607. The substation equipment illustrated is also of a well-known type.

15 *Arrangement of number indicating devices at manual offices.*

Common to and associated with each group of trunks (Fig. 16) appearing before an operator is an allotter of cord finders, an 20 allotter of assignment lamps and called line number indicators, a plurality of cord finders with each of which is associated a decimal distributor (Fig. 17). Individual to each decimal distributor is a set of four 25 switching devices herein termed "decimal registers," and a set of four groups of signaling lamps designated thousands, hundreds, tens and units herein termed "called line number indicators" (Fig. 18) which 30 are common to the decimal registers of an operator's position.

The allotter of cord finders is similar to the allotter of line finders (Fig. 4) as hereinbefore described, and comprises a plurality of sets of passive contacts 1701, 1702, one set for each associated cord finder with which coöperate the brushes W^{53} , W^{54} respectively adapted to be positioned in response to energizations of the motor magnet 35 MM^4 , under the control of the relay T^4 . Likewise the allotters of assignment lamps and called line number indicators are similar to the allotter of line finders (Fig. 4). They are provided with as many sets of 40 passive contacts 1703 to 1708 inclusive, with which coöperate brushes W^{55} to W^{60} inclusive, as there are associated decimal registers. The brushes W^{55} to W^{60} inclusive are 45 rotated step by step into and out of connection with their associated contacts in response to energizations of the motor magnet MM^5 , under the control of the test relay T^5 .

The cord finder is structurally similar to 50 the described connecting circuit finders of Fig. 8, being provided with a plurality of sets of contacts 1709 to 1713 inclusive divided into rows or minor groups corresponding to the minor grouping of the 55 trunk circuits (Fig. 16) which, as stated, may be five groups of ten each per position. The brushes W^{61} to W^{65} inclusive are automatically rotated step by step in their primary selecting direction responsive to energizations of the motor magnet PM^{10} , under

the control of the test relay PT^{10} , until the brush W^{61} engages a group contact 1709 corresponding to the minor group in which is included the terminals of a trunk line of Fig. 16 awaiting selection. Thereupon the 70 primary selecting operation terminates and the brushes W^{62} to W^{65} inclusive are automatically rotated step by step, responsive to energizations of the motor magnet SM^{10} , under the control of the relay ST^{10} , in their 75 secondary selecting operation, until the brush W^{62} engages a contact 1710, the multiple terminal of a trunk circuit (Fig. 16) awaiting selection, when the secondary selecting operation terminates and the brushes 80 W^{62} to W^{65} inclusive come to rest in engagement with the associated contacts 1710 to 1713 inclusive, terminals of the selected trunk line, and thereby extend the connecting circuit (Fig. 7), then in connection with 85 the trunk circuit (Fig. 16), to connection with the decimal distributor (Fig. 17).

The contacts of PON^{10} move to their alternate positions when the brushes leave normal position and are not restored until the 90 return of the brushes to the position immediately above normal. The normal contact of SON^{10} is interrupted and its alternate contact closed when the brushes W^{62} to W^{65} inclusive are started on their secondary 95 selecting operation and is not restored until the return of the brushes to normal position.

Associated with each of the cord finders is a release relay RR^{10} and a release control relay RC^{10} which operate as will be hereinafter described.

The decimal distributors are similar to the allotters described, each comprising six sets of passive contacts 1714, 1715, 1716, with which coöperate the brushes W^{66} , W^{67} , W^{68} respectively, adapted to be positioned responsive to automatic energizations of the motor magnet MM^{12} , under the control of the relays 105 1717, 1718, 1719, individual to and associated therewith. Each decimal distributor, in addition, is provided with a contact 1720 which is closed at all positions of the brushes, except their first or normal position, and a contact 1721 which is closed 110 at the last or sixth position only of the brushes.

The relay 1717 is responsive to the impulses transmitted from the impulse transmitters (Fig. 9) and controls the energizations and deenergizations of relays 1718, 1719, which are slow to release their armatures, and the rotation of the brushes of each section of the associated decimal register (Fig. 18), now to be described.

Any suitable structure may be utilized for the sections of the decimal register. They may be, in so far as the apparatus required, similar to the sections of the impulse transmitters illustrated in Figs. 22 to 130

33 inclusive. These registers are, as previously stated, divided into four sections designated thousands, hundreds, tens and units, corresponding to the thousands, hundreds, tens and units digits of the numerical numbers of the substations of the manual offices.

The thousands section comprises a plurality of sets of contacts 1801 with which 10 coöperates the brush W^{60} ; the hundreds section, a plurality of sets of contacts 1802, 1803 with which coöperate brushes W^{70} , W^{71} respectively; the tens section, a plurality of contacts 1804 with which coöperates 15 brush W^{72} ; the units section, a plurality of passive contacts 1805 with which coöperates the brush W^{73} .

The brushes of each section are rotated 20 step by step in their setting operation responsive to impulses of current transmitted from the corresponding sections of the impulse transmitters (Fig. 9), repeated through a contact of relay 1717 (Fig. 17), through the winding of the motor magnets 25 MM^{12} , to move the brushes to connection with the desired passive contacts, terminals of the indicator signal lamps 1806, corresponding to the thousands, hundreds, tens, and units keys (Fig. 9, Parts 1 and 2) actuated, and which correspond to the numerical designation of desired called substations to cause the illumination of such lamps, to 30 visually indicate to the operators the numbers of the called substations.

35 Each section of the decimal registers is provided with a release magnet RM^{12} and the contacts ON, which are closed at all positions of the associated brush or brushes, except normal. The tens section is, in addition, 40 provided with a contact 1807, which is closed at all positions of the brush W^{72} from 1 to 10 inclusive, and a contact 1808 which is closed at all positions of the brush W^{72} from 11 to 20 inclusive.

45 *Arrangement of manual incoming trunks, selectors and finder switches.*

Referring now to the trunk lines employed in establishing connection between 50 calling subscribers having lines terminating in manual offices and called subscribers having lines terminating in automatic call distributing offices which are illustrated in Fig. 19, Parts 1 and 2, the outgoing terminals of these trunks, which are located at the manual offices, are not shown, but it is to be understood they are of the usual spring-jack construction and located in the manual switchboards at the offices in which 55 60 terminate the lines of the manual subscribers. These trunk line circuits appear before the operators at the automatic call distributing offices in the form of keys and signal lamps, each being provided with—

65 (a) A key 1901, herein termed "assign-

ment key", which is non-locking and when actuated from normal will cause an allotted one of a plurality of associated manual incoming trunk connecting circuit finders (Fig. 20) to start to automatically select the 70 corresponding trunk and thereupon connect with such trunk line an impulse transmitter associated with and individual to such manual incoming trunk line finder.

(b) A key 1902, herein termed "holding 75 key", which is locking and when actuated from normal acts to hold all apparatus then associated with its trunk in its then adjusted position, in which condition the apparatus will remain so long as the key is in its off- 80 normal actuated position, irrespective of any action by the operator at the manual office to which the trunk leads and terminates in. It will be understood from the description hereinafter of the operation of 85 the system of the invention that the restoration of the apparatus associated with the trunks at the automatic call distributing offices will ordinarily be automatically accomplished upon disconnection by the operators at the manual offices. The key 1902 is provided for preventing such automatic disconnection.

(c) A key 1903, herein termed "disconnect key", which is non-locking and when 95 actuated from normal will cause all apparatus, at the time operatively associated with the corresponding trunk, to be automatically restored to normal.

(d) A lamp 1904, herein designated 100 "guard lamp".

(e) A lamp 1905, herein designated "busy lamp".

The lamps 1904 and 1905 visually indicate to the operator the conditions during 105 the establishment of and during the existence of a connection.

Each manual incoming trunk line circuit is provided with a relay 1907 having the characteristics of the relays 1511 and 1618 110 previously described; a supervisory relay 1908; a differentially wound relay 1915, which has the characteristics of relays 1108 and 1615 previously described; a relay 115 GTR^3 which has the characteristics of the GTR^3 relays previously described; a selector switch, herein termed "manual incoming trunk selector", which is similar to the incoming trunk selectors of Fig. 11 and Fig. 15, provided with passive contacts 1917 to 120 1920 inclusive, with which coöperate brushes W^{74} to W^{77} inclusive respectively. The connections of the passive contacts of these switches are as described in connection with the local incoming selectors and interoffice 125 incoming selectors.

The magnets PM^{12} , SM^{12} , relays PT^{12} , ST^{12} , RR^{12} , contacts PON^{12} , SON^{12} , SOR^{12} , of the manual incoming selectors are likewise similar to and operate as described in 130

connection with the mentioned incoming selectors. In addition, each manual incoming trunk line is provided with a repeating coil 1906 and a plurality of relays which 5 function as will be described in connection with the operation of the system.

In order that the manual incoming trunk lines of each group appearing before an operator may be selected by the manual incoming trunk finders, and the impulse transmitters associated therewith placed in connection with the desired one of such trunk line circuits without effective delay, they are divided into minor groups in any desirable 10 manner. For the purpose of illustration it will be supposed that each group appearing before an operator comprises fifty circuits, and that they are divided into five minor groups of ten each, termed "finder groups 15 of manual incoming trunk lines". For each such group, a relay GBC¹² (Fig. 20) is provided, adapted, upon the actuation of the assignment key 1901 of a trunk line of the associated minor group, to be energized and 20 control the starting of the allotted one of the manual incoming trunk finders to select, first, the corresponding minor group, and thereupon to select the particular manual incoming trunk line of the assignment key 25 1901 actuated, to connect the associated impulse transmitter therewith.

Common to and associated with each group of manual incoming trunk lines appearing before an operator there is provided—

(a) A plurality of herein termed "manual incoming trunk finder switches" (Fig. 20) similar to the described connecting circuit finders (Fig. 8), with each of which 40 is associated an impulse transmitter and a section of a recorder (Fig. 21, Parts 1 and 2), each adapted when idle and allotted, responsive to the actuation of the assignment key of any one of the trunk lines of the 45 associated group, to be automatically started to rotate its brushes W⁸⁴, W⁸⁵, W⁸⁶, W⁸⁷, W⁸⁸ responsive to automatic energizations of magnet PM¹³ under the control of relay PT¹³, until the brush W⁸⁴ engages a passive 50 group test contact 2004, multiply connected to the normal contact 2003 of the relay GBC¹² of the minor group, in which is included the manual incoming trunk line of which the key 1901 has been actuated from 55 normal, and to thereafter automatically rotate its brushes W⁸⁵ to W⁸⁸ inclusive responsive to energizations of magnet SM¹³, under control of relay ST¹³, step by step into and out of connection with the associated 60 sets of passive contacts 2005, 2006, 2007, 2008 respectively of the row or minor group until the set, to which is multiply connected the terminals of the manual incoming trunk line desired is engaged, when they are

brought to rest in connection therewith and 65 extend the associated impulse transmitter to connection with such selected manual incoming trunk line.

(b) An allotter (Fig. 21, Part 1) which is structurally similar to the allotters hereinbefore described and comprises a plurality of sets of contacts 2101, 2102, 2103, 2104, one set for each manual incoming trunk finder, with which coöperate brushes W⁸⁰, W⁸¹, W⁸², W⁸³, adapted to be positioned responsive to automatic energizations of its motor magnet MM¹⁴ under the control of the relay T¹⁴.

(c) A set of recording keys 2106 divided into four groups of ten each, designated 80 thousands, hundreds, tens and units respectively, adapted when a key in each group is actuated from normal to cause the allotted division of the associated recorder to close contacts 2108 corresponding to the 85 actuated key in each section, which in turn causes the impulse transmitter associated with the allotted manual incoming trunk line finder to assume positions corresponding to the contacts 2108 closed. These recording keys may be, as stated in connection with the recording keys of Fig. 9, of any desired construction, and are adapted when actuated from normal to be locked until the contact of each section of the allotted 90 division of the recorder has closed the contacts corresponding thereto, whereupon the restoring magnets RM¹⁴ of each group are energized, which causes the restoration to normal of the keys actuated.

(d) A device herein termed "recorder," which may be of any desired construction, a preferred arrangement being illustrated in Figs. 34, 35 and 36 to be hereinafter described, which is common to the recording keys 2106 and has a magnet 2112 for each key of each group of recording keys. This device is divided into a plurality of as many divisions as there are impulse transmitters associated with the group of manual incoming trunks. For each division there is provided a connecting magnet CM¹⁵ and a restoring magnet RM¹⁵. Each division is divided into four sections, herein termed thousands, hundreds, tens and units sections, each 105 comprising ten sets of contacts 2108. The first, third, fourth, fifth, seventh and ninth set of the contacts 2108 of the hundreds section of each division of the recorder comprise two contacts each and all other sets 110 of the contacts 2108 comprise a single contact per set. Common to the magnets 2112 of each section, and adapted to be closed responsive to the energization of any one thereof, there is provided a contact 2113. 115 The arrangement is such that upon the actuation of a key 2106 in each group, the corresponding magnets 2112 will be energized.

gized, the contacts 2113 of each section closed and circuit established for the magnet CM^{15} of the allotted division which will close a set of contacts 2108 in each section corresponding to the keys actuated. Upon the energization of magnet CM^{15} , circuits are established which cause the energization of the release magnets RM^{14} of each group to restore the actuated keys to their normal positions and substantially simultaneously therewith circuits are established which cause the brushes W^{20} to W^{23} inclusive of the allotter of manual incoming trunk finders to be moved from connection with their then engaged set of passive contacts to connection with a set of passive contacts, the terminals of a manual incoming trunk line finder then in normal position and with which is associated an impulse transmitter then in normal position.

(e) A plurality of impulse transmitters (Fig. 21, Parts 1 and 2) each associated with a manual incoming trunk line finder (Fig. 20) and each divided into four sections designated thousands, hundreds, tens and units, corresponding to the grouping of the recording keys 2106, which are substantially as described in connection with the numerical sections of the impulse transmitters of Fig. 9 and are structurally as illustrated and described in Figs. 22 to 33 inclusive. Each section comprises a brush $W^{20'}$, adapted, when a contact 2108 of each section of the associated division of the recorder is actuated from normal, to be automatically rotated step by step into and out of engagement with its associated row of passive contacts 911, terminals of the corresponding contacts 2108 of the corresponding section of the associated division of the recorder, until the brush $W^{20'}$ engages a passive contact 911 connected with the contact 2108 then closed, when the brush comes to rest in engagement therewith. The brushes of each section of these impulse transmitters are, as described in connection with the impulse transmitters of Fig. 9, simultaneously started on their selecting operation, and when the brush of each section engages its passive contact leading to and connecting with a closed contact 2108 of the corresponding section of the recorder, a circuit is established which, in the manner hereinafter to be described, causes the energization of the restoring magnet RM^{15} of the corresponding division of the recorder, resulting in the interruption of the closed contacts of each section thereof, following which the brushes $W^{20'}$ of each section are caused to be sequentially retrograded to their normal position, each transmitting, during such movement to the directly actuated manual incoming trunk line selector, hundreds selector and final selector, series of impulses of

current corresponding to the passive contacts to which the brushes were, in their setting operation, adjusted.

Mechanical arrangement of recorders.

Referring now to Fig. 34, which is a plan view with certain parts removed; Fig. 35, a front elevation section along the line 35, Fig. 34; and Fig. 36, a section along the line 36 of Fig. 34 illustrating a preferred structural arrangement of the recorders described in connection with Fig. 21, Parts 1 and 2, adapted to record the numbers of called substations responsive to actuations of the recording keys also described in connection with Fig. 21, Parts 1 and 2, the frame members 2115 are rigidly secured together by angles 2127 and are substantially parallel. Rigidly mounted between the members 2115 are supporting plates 2116, there being as many plates 2116 as there are divisions of the recorder, to each of which is secured the elements of contacts 2108 of each section of the corresponding division, and the elements of the contact 2129 (not shown in the drawing), the passive members of which are rigidly secured thereto and the movable members pivotally mounted thereon by means of the shouldered studs 2117 and arms 2118.

The rods 2119 are journaled in plates 2120 and adapted to be oscillated vertically responsive to the actuations of the magnets 2112. The rocker arms 2121 are each provided with a retractile spring, adapted to maintain them normally in the position shown and rotatably secured to the rods 2119, there being as many arms 2121 secured to each rod 2118 as there are divisions of the recorder. The rods 2119 are each held in their normal illustrated positions against the tension of a leaf spring 2122 which rests against a pin 2123. Associated with each leaf spring 2122 are the contact springs 2124, 2125 corresponding to contacts 2113 (Fig. 21, Parts 1 and 2).

The plates 2126 are mounted on the angles 2127 and carry the magnets 2112 as shown in Figs. 35, 36. The magnets CM^{15} are mounted on the left-hand frame member 2115 (Fig. 34), to each of which is secured a rod 2128 adapted to engage the rocker arms 2121 and rotate them about their pivots to engage the arms 2118, and rotate the movable members of the contacts 2108 and 2129 into connection with their associated passive members. The armature and rod 2128 of each magnet CM^{15} are adapted to be restored, under tension of a suitable leaf spring engaging an angular extension of the armature, as shown in Fig. 34. Likewise, the restoring magnets RM^{15} are mounted on the left-hand frame member 2115 (Fig. 34), with each of which is associated

an arm 2130 adapted to engage the rearward extension of each of the arms 2118 of the corresponding division to rotate the movable elements of contacts 2108 and 2129 out of connection with their associated passive elements. The armatures of the magnets RM¹⁵ and the rods 2130 are each restored upon de-energization of the associated magnet RM¹⁵ to normal under tension of a suitable leaf 10 spring as shown in Fig. 34.

The operation of the device is such that upon the energization of a magnet 2112 in each section, the associated rods 2119 are moved vertically upward, bringing the 15 rocker arms 2120 in alignment with the rearward extension of the associated arms 2118, whereupon, when the magnet CM¹⁵ of the allotted division is energized and its rod 2128 moved to the right, the corresponding 20 rocker arms 2121, of the rods 2119 elevated, are engaged and rocked about their pivots into engagement with the corresponding arms 2118, resulting in the connection of the movable elements with the passive elements 25 of the corresponding contacts 2108 and 2129. Thereafter upon the de-energization of the magnets 2112, responsive to restoration of the recording keys, the rods 2119 are moved vertically downward to normal and the actuated ones of the rocker arms 2120 rotated to normal, following which, by the opening 30 of the contacts 2113, circuit through the winding of the actuated magnet CM¹⁵ is interrupted, the magnet de-energized and the rod 2128 restored, leaving the movable 35 elements of contacts 2108 and 2129 in engagement with their passive elements.

Upon the energization of magnet RM¹⁵ of a division in which the movable element, or 40 elements, of a set of contacts 2108 of each section and the movable element of contact 2129 have been connected with their passive elements, the associated rod 2130 will be moved to the right and engage the arms 2118 of all contacts 2108 and contact 2129, in 45 which the movable elements are in connection with the passive elements, and restore same to normal. Thereafter upon the de-energization of the magnet RM¹⁵, the associated arm 2130 is, under the tension of the 50 associated leaf spring, moved to the left to its normal position.

Arrangement of batteries in automatic call distributing offices.

For the purpose of simplifying the circuit diagrams, a plurality of batteries are symbolically illustrated. It is to be understood, however, that each automatic call distributing office need comprise two batteries only, one of which has its positive pole grounded and will hereinafter be referred to as the negative battery. The other of the two batteries has its negative pole 55 grounded and will, when hereinafter referred to, be designated as positive battery.

Description of operation—establishment of connection between a calling line and an operator's position.

Having described the arrangement of the apparatus and circuits employed for illustrating the features of this invention, their operation will now be referred to in detail.

Considering first intraoffice connections 70 which employ circuits and apparatus illustrated in Figs. 1 to 13 inclusive, arranged as shown in Fig. 37, it will be assumed that a substation of Fig. 1 or Fig. 2 or Fig. 3, at the left of the diagram, desires connection with a substation of Fig. 1 or Fig. 2 or Fig. 3, at the right of the diagram. Upon the initiation of a call, a circuit is established from ground, winding of relay LR or LR² or LR³, contact 1 of relay CO or CO² or CO³, line conductor 101 or 201 or 301 through the instrumentalities of the substation, returning over line conductor 102 or 202 or 302, contact 2 of relay CO or CO² or CO³, lower winding of relay LR or LR² or LR³, negative battery to ground, which energizes the relay LR, LR² or LR³ as the case may be, thereby interrupting its normal contact and closing its alternate contact.

The opening of the normal contact 95 of relay LR, LR² or LR³ removes ground from connection with the conductor multiply connected with test contacts 411 of the line finders (Fig. 4), which renders the line

selectable by the line finders of the associated secondary group. The closure of alternate contact of relay LR or LR² or LR³ establishes a circuit traceable from ground, alternate contact of relay LR, LR² or LR³, common conductor, winding of relay GBC of the minor group, negative battery to ground, which energizes the relay GBC, resulting in the interruption of its normal contact and the closure of its alternate contact.

The interruption of the normal contact of relay GBC disconnects ground from the multiply connected group test contacts 415 of the corresponding minor group or row. The closure of the alternate contact of relay GBC establishes a circuit 105

traceable from ground, alternate contact of relay GBC, common conductor 420, normal contact of relay T, brush W, its engaged passive contact 419 of the allotter (Fig. 4), terminals of an idle line finder and its 110

linked connecting circuit selector, thence in multiple through the windings of relays PT and PT' of the line finder and PT' of the connecting circuit selector (Fig. 5). The circuit from contact 419 for the relay PT of the line 115

finder may be traced from the normal contact of PON, winding of relay PT, negative battery to ground, and for the relay PT',

from the normal contact of PON, winding of relay PT', negative battery to ground, and for the relay PT,

- from normal contact of PON', winding of relay PT', negative battery, to ground, which causes the energization of the relays PT and PT' resulting, in respect to relay
- 5 PT, in the opening of its normal contact and the closure of its alternate contacts, establishing a vibratory circuit traceable from ground, right-hand alternate contact of PT, interrupter contact and winding of PM,
- 10 negative battery, to ground, for the motor magnet PM, which responds and by the attraction of its armature moves brushes W₁ to W₅ inclusive one step in their primary selecting direction, establishing connection
- 15 of brush W₁ with its first contact 415, during which movement of the brushes the initial energizing circuit of the relay PT, traced through the normal contact of PON, is interrupted, but unless the terminals of
- 20 the line of the calling substation be included in the first minor group of fifteen lines, a maintaining circuit, traceable from ground, normal contact of relay GBC of the first minor group, to passive contact 415, brush
- 25 W₁, left-hand alternate contact of relay PT, negative battery, to ground, is established, which maintains the relay PT in its energized position with its alternate contacts closed. Hence, the traced circuit for the
- 30 magnet PM will be maintained and the magnet continued to be energized and de-energized, responsive thereto, moving the brushes W₁ to W₅ inclusive step by step from row to row until the brush W₁ engages
- 35 the contact 415 of the row of minor group of lines, in which is included multiple terminals of the line of the substation calling, whereupon, owing to the energization of the relay GBC of the minor group, the holding
- 40 circuit, traced for the relay PT, will be interrupted, its alternate contacts opened and the traced circuit for the magnet PM interrupted, which leaves the brush W₁ in connection with the contact 415, corresponding
- 45 to the minor group of the line of the calling substation, and the brushes W₂ to W₅ inclusive opposite the minor group or row of fifteen sets of contacts 411 to 414 inclusive, multiple terminals of the lines of the minor
- 50 group in which is included the terminals of the line of the substation calling.
- Following the de-energization of relay PT, a circuit traceable from ground, right hand normal contact of relay PT, alternate contact of PON, contact of SON, right-hand winding of relay ST, negative battery, to ground, is established for the relay ST which is energized, resulting in the interruption of its normal contacts and the
- 55 closure of its alternate contacts, establishing a vibratory circuit for the magnet SM, from ground, alternate contact 1 of relay ST, interrupter contact 1 and winding of motor magnet SM, negative battery, to ground,
- 60 and in multiple therewith through inter-
- rupter contact 2 of SM and left-hand winding of relay ST, negative battery, to ground, which establishes a holding circuit for the relay ST to maintain the relay energized during the passage of the brushes W₂ to W₅ inclusive from connection with one set of their passive contacts to connection with their succeeding set. The magnet SM responding, by the attraction of its armature, the brushes W₂, W₃, W₄ and W₅, are moved into engagement with the first set of contacts 411, 412, 413 and 414 respectively, the multiple terminals of the first line of the minor group, during which movement of the brushes by the opening of contact of SON, the traced initial energizing circuit through the right-hand winding of relay ST is interrupted, but a maintaining circuit is, unless the line of the calling substation be connected with the first set of contacts, 411 to 414 inclusive, established, traceable, if the line be idle, from ground, normal contact of relay LR or LR² or LR³, thence over the test conductor to multiple connection with the first contact 411, brush W₂ then in connection therewith, left-hand alternate contact of relay ST, left-hand normal contact of relay RR, right-hand winding of relay ST, negative battery, to ground; or, if the line be busy as a calling line, from ground, positive battery (Fig. 7, Part 2), winding of resistance coil 749, alternate contact 2 of relay 747, alternate contact 4 of relay 748, normal contact of key 708, left-hand normal contact of key 705 to passive contact 503 and brush W₁₀ in engagement therewith, normal contact 2 of relay ST', normal contact 1 of polarized relay 506 (Fig. 5), left-hand normal contact of relay ST, brush W₂, multiply connected contact 411 of some other line finder of the secondary group, contact 411, brush W₂, and thence over the previously traced circuit through the right-hand winding of the relay ST. Or, if the line be busy as a called line, from ground, alternate contact 1 of LTR (Fig. 13), wiper W₃₉, contact 1304, thence to the contact 411, brush W₂, over the previously traced circuit, through the right-hand winding of relay ST, negative battery, to ground. The circuit through the relay ST being maintained, the magnet SM will continue to be energized and de-energized, causing the brushes W₂ to W₅ inclusive to move, step by step, into and out of engagement with their associated contacts 411 to 414 inclusive, until the brush W₅ engages the test contact terminal 411 of the line of the calling substation, when the maintaining circuit through the relay ST, by the opening of the normal contact of the relay LR or LR² or LR³, is interrupted, resulting in the opening of the alternate contacts of the relay ST and thereby the interruption of the traced vibratory circuits through the wind-

ing of motor-magnet SM and through the right-hand winding of relay ST.

The arrangement of the contacts 411 to 414 inclusive is such that their associated 5 brushes W_2 to W_5 inclusive respectively, break connection with one contact before connecting with a succeeding contact; thus, the holding circuit through the right-hand winding of the relay ST, during each energization of the magnet SM, is interrupted, but the relay is held energized over the traced circuit, including the interrupter contact 2 of the motormagnet SM. When the brushes W_2 to W_5 inclusive come to rest in 10 engagement with the contacts 411 to 414 respectively, the multiply connected terminals of the line of the calling substation, following the deenergization of relay ST, a circuit is established from ground, winding 15 of resistance coil 507, normal contact 2 of relay 508, contact 3 of relay ST, brush W_3 , the engaged contact 412, winding of relay CO or CO^2 , negative battery, to ground, or winding of CO^2 , positive battery to ground, 20 whereby the relay CO or CO^2 or CO^3 is energized and its contacts opened, which 25 interrupts traced circuit through the relay LR or LR^2 or LR^3 which is deenergized, its alternate contact opened and its normal contact closed, resulting, unless there be another 30 substation of a line of the same minor group of fifteen lines then calling, in the interruption of the previously traced circuit through the relay GBC, which will be deenergized, 35 its alternate contact opened and its normal contact closed, restoring the corresponding contacts 415 to connection with ground, and thus rendering the minor group unselectable by the associated line finders. 40

Responsive to the deenergization of relay ST, ground is connected with the test contact 411 of the line of the calling substation, from ground, normal contact 3 of relay RR, normal contact 1 of relay ST, brush W_2 , 45 is engaged passive test contact 411, which renders the line unselectable by any other line finder of the associated secondary group, and unselectable by any of the group of final selectors (Fig. 13), to the passive 50 contacts of which the called terminals of the line are multiply connected.

The energization of relay PT', over the 55 previously traced circuit in multiple with the relay PT of the line finder, establishes a vibratory circuit for the motormagnet PM', from ground, left-hand alternate contact of relay PT', interrupter contact and winding of magnet PM', negative battery, to ground, which responds and moves the 60 brushes W_s to W_{12} inclusive one step from normal in the primary selecting operation, whereby brush W_s is connected with the first group test contact 501, corresponding to and multiply connected with the contacts of relays 714—730—733 and GBC' (Fig. 7, Part

1), and the brushes W_s to W_{12} inclusive, opposite the first row of the sets of contacts 502 to 505 respectively, multiply connected terminals of a minor group of connecting circuits appearing before an operator, during 70 which movement of the brushes the initial energizing circuit for the relay PT' is, by the opening of the normal contact of PON¹, interrupted, and if the first row or minor group of passive contacts includes the multiple terminals of an idle connecting circuit and appearing before an idle operator, the relay PT' will be deenergized. It is assumed, however, that each and all of the connecting circuits multiply connected with 75 the passive contacts of the first row or minor group is in use, or that the operator before whom they appear is busy. The contact 501 will, therefore, be multiply connected with ground through an alternate contact of relay 80 714, or 730 or 733, or GBC', with the result that when brush W_s engages the contact 501 of the first row, a maintaining circuit from ground as traced, to contact 501, brush W_s in engagement therewith, right-hand 85 alternate contact and winding of PT', negative battery, to ground, is established, the relay maintained energized and the traced circuit for the magnet PT' maintained, which responding moves the brushes step 90 by step until the brush W_s engages a contact 501, the multiple test terminal of a minor group of connecting circuits, included in which is an idle connecting circuit appearing before an operator then idle, when 95 the traced maintaining circuit for the relay PT' is, owing to the absence of ground connection with the contact 501, interrupted, the relay deenergized, its alternate contacts 100 opened and its normal contact closed, which 105 interrupts the traced vibratory circuit through the motor magnet PM' and connects ground through brush W_s to the corresponding group test contacts 501 and 601 of each 110 connecting circuit selector and secondary connecting circuit selector, to the passive contacts of which are connected the selective terminals of the connecting circuits of the minor group, traceable from ground, left-hand normal contact of relay PT', alternate 115 contact of PON', normal contact 2 of relay RR', contact of POR', right-hand normal contact of PT', brush W_s , contact 501, which prevents, during the existence of such ground connection, the selection of the minor group 120 of connecting circuits by any other connecting circuit selector or secondary connecting circuit selector (Fig. 6). The deenergization of relay PT' also establishes a circuit from ground, left-hand normal contact of 125 relay PT', alternate contact of PON', normal contact of SON', left-hand winding of relay ST', which energizes the relay ST' and establishes a vibratory circuit for the magnet SM' from ground, normal contact 130

3 of relay 509, alternate contact 3 of relay ST', interrupter contacts, winding of relay SM' to negative battery, and right-hand winding of relay ST', negative battery to ground, which holds relay ST' energized during the passage of the brush W_{10} from connection with one contact 503 to the next succeeding contact; and responsive to its traced vibratory circuit, the magnet SM' is actuated and the brushes W_9 to W_{12} inclusive moved to connection with the first set of passive contacts 502 to 505 inclusive of the selected row, the multiple terminals of the first connecting circuit of the corresponding minor group, during which movement of the brushes the normal contact of SON' is interrupted, and unless the connecting circuit connected therewith be busy, upon the completion of the stroke of the armature of SM' circuit will be interrupted for the relay ST', which will deenergize, open its alternate contacts and close its normal contacts.

Assuming the connecting circuit connected with the first set of contacts 502 to 505 to be busy, then the multiply connected test contact 503 will be connected with ground traceable from normal contact 2 of relay 747, alternate contact 4 of relay 748, normal contact 1 of key 708, normal contact 1 of key 705, to contact 503, or from ground, contact 411, wiper W_2 , normal contact 1 of ST, contact 1 of relay 506, normal contact 2 of relay ST', brush W_{10} , corresponding multiply connected contact 503 of some other connecting circuit selector; or, should the relay 506 of some other connecting circuit selector connected with such connecting circuit be energized and its contacts opened, then the ground connection would include the windings of such relay 506; or, if the relay 747 be energized, the multiple test contact 503 would be connected with positive battery through the winding of resistance coil 749 and alternate contact of relay 747, and thence over the previously traced path. As a result, the relay ST' will be maintained energized over the circuit as traced to the contact 503, brush W_{10} , alternate contact 2 of relay ST', normal contact 3 of relay RR', left-hand winding of relay ST', negative battery, to ground, which will maintain the traced vibratory circuit through the motor-magnet SM' which, responding, will move the brushes W_9 to W_{12} step by step into and out of engagement with the associated passive contacts 502 to 505 inclusive, respectively, terminals of connecting circuits of the selected minor group, until the brush W_{10} engages the test terminal 503 of a connecting circuit then idle, when the traced maintaining circuit through the relay ST' will be, owing to the absence of ground connection or the connection of positive battery B to the passive contact 503, interrupted, with the re-

sult that upon the completion of the stroke of the armature of magnet SM', by the opening of its interrupter contacts, the traced circuit, through the winding of magnet SM' and through the right-hand winding of relay ST', will be interrupted, the relay ST' deenergized, its alternate contacts opened and its normal contacts closed, which will interrupt the vibratory circuit through the motor-magnet SM', whereby the brushes W_9 to W_{12} inclusive will be left in connection with the passage contacts 502 to 505 inclusive, the multiple terminals of the thus selected idle connecting circuit, and thereby extend the line of the calling substation to a connection with such connecting circuit.

By the closure of the normal contact 2 of relay ST', following its deenergization, ground is connected to the corresponding test contact 503 of each connecting circuit selector and to the test contact 603 of each secondary connecting circuit selector, to the passive contacts of which are multiply connected the selective terminals of the connecting circuit, which prevents selection of the connecting circuit by any of the connecting circuit selectors or secondary connecting circuit selectors. Such connection for the contact 503 may be traced from ground, normal contact 3 of relay RR, contact 1 of 506, normal contact 2 of ST', brush W_{10} to contact 503, or, from ground, normal contact of relay LR, or LR^2 , or LR^3 , through lamp LL or LL^2 or lamps LL^3 as the case may be, passive contact 411, brush W_2 in engagement therewith, normal contact 1 of ST, of the linked line finder, thence over the previously traced path to contact 503.

Following the deenergization of relay ST' when the brush of I' engages its live segment, the initial energizing circuit of relay 509 is established, which includes ground, the live segment and brush of interrupter I', alternate contact of SON', normal contact 4 of relay RR', contact 1 of relay ST', right-hand winding of relay 509, normal contact 3 of relay 510, brush W_{12} , its engaged passive contact 505 of the selected connecting circuit, normal contact 3 of key 705, normal contact 2 of relay 750, winding of supervisory relay 751 and lower left-hand winding of repeating coil 753, negative battery, to ground.

The relay 509 responding, a holding circuit therefor is established from ground, normal contact 1 of relay RR', alternate contact 2 and left-hand winding of relay 509, negative battery, to ground. The traced initial energizing circuit which included the interrupter I' for the relay 509, being only momentary, and followed thereafter by the connection of the brush of interrupter I_2 with its live segments, a circuit is established from ground, live segments and brush of I_2 , alternate contact 1 of 509, normal contact 2

of 510, brush W_{11} , engaged passive contact 504, normal contact 2 of key 705, normal contact 1 of relay 750, normal contact 1 of relay 752, winding of motormagnet MM' of 5 the class of service register of the associated connecting circuit, negative battery to ground. The magnet MM' responding thereto, rotates the brushes W_{18} step by step, responsive to the connection and disconnection 10 of the brush of I_2 with each of its live segments, causing one of the brushes to connect with the passive contact 710, corresponding to the class of the line of the calling substation, which is multiply connected 15 with a corresponding lamp 734.

Immediately following the adjustment of a brush W^{18} to connection with a contact 710, connection is again established between the brush and live segment of I' , establishing 20 the traced circuit through the winding of relay 751, which responds and completes the initial energizing circuit for the relay 752 from ground, key 707, normal contact 4 of key 706, alternate contact of relay 751, 25 contact 713 of the class of service register (contact 713 closed at all positions of brushes W^{18} except normal), winding of relay 752, negative battery, to ground, which is actuated, establishing a holding circuit 30 therefor from ground, contact of 707, normal contact 4 of 706, alternate contact 2 and winding of 752, negative battery, to ground, which holds the relay in its energized position so long as keys 706 and 707 remain in 35 their normal position. The closure of alternate contact 3 of relay 752 establishes the initial energizing circuit for the relay 748, from ground, alternate contact 3 of 752, winding of relay 748, negative battery, to 40 ground.

Responsive to the closure of alternate contact 4 of relay 752, circuit is established for the relay 510, from ground, contact 1 of relay 747, alternate contact 4 of relay 752, 45 normal contact 3 of relay 750, passive contact 502, brush W^9 in connection therewith, normal contact 3 of relay ST' , alternate contact 3 of relay 509, windings of relay 510, (contact of POR' now open), normal contact 2 of relay 506, and in multiple therewith, from ground, winding of resistance coil 507, normal contact of relay 508 to normal contact of relay ST , thence through brush W^3 , engaged contact 412, winding of 55 relay CO , or CO^2 , or CO^3 , negative battery, to ground, resulting in the energization of relay 510, and by the closure of its alternate contacts 2 and 3 in the extension of the talking strands of the line, as indicated by 60 the heavily drawn lines, to connection, through the brushes W^4 and W^5 in engagement with the passive contacts 413 and 414, multiple terminals of the calling line, alternate contacts 2 and 3 of 510, through 65 brushes W^{11} and W^{12} in engagement with

passive contacts 504 and 505 respectively, multiple terminals of the connecting circuit; and establishes a circuit for the relay 508, from ground alternate contact 1 of 510, winding of relay 508, negative battery, to 70 ground, which is energized, interrupting, by the opening of its normal contact 2, the winding of resistance coil 507 from multiple connection with relay 510, and by closure of its alternate contacts 1 and 3 establishes 75 the initial energizing circuits of the relay RR of the line finder and RR' of the connecting circuit selector, which for the relay RR may be traced from ground, right-hand normal contact of relay PT , alternate contact of PON , alternate contact 1 of 508, winding of relay RR , negative battery, to ground; and for the relay RR' from ground left-hand normal contact of PT' , alternate contact of PON' , alternate contact 3 of 508, 85 winding of relay RR' , negative battery, to ground.

The energization of the relay RR removes the existing ground connection, through its normal contact 3, from the brush W^9 , and 90 establishes a circuit from ground, its alternate contact 3, passive contact 418, brush W^6 in connection therewith, winding of relay T of the allotter, negative battery, to ground, which effects the energization of 95 the relay T , which, by the closure of its left-hand alternate contact, establishes the vibratory circuit through the winding of motormagnet MM from ground, left-hand alternate contact of T , interrupter contact and 100 winding of motormagnet MM , negative battery, to ground, which responds and rotates the brushes W^6 and W^7 out of connection with the then engaged contacts 418 and 419 respectively, and into and out of connection 105 with corresponding contacts leading to other linked line finders and connecting circuit selectors of the associated group until the contacts 418 and 419, corresponding to a line finder and associated connected circuit 110 selector then idle, are engaged, when the circuit of the relay T , as a result of the absence of ground connection with contact 418, is interrupted, the relay deenergized, its alternate contact opened, interrupting the vibratory circuit through the winding of motormagnet MM , preventing its further actuation, leaving the brushes in connection with the then engaged passive contacts, whereby the hereinbefore traced starting circuit 115 through the alternate contact of the relays GBC may be established to initiate the starting of the corresponding line finder and linked connecting circuit selector responsive to the next succeeding call from a substation 120 of any line of the associated secondary group.

By the closure of alternate contact 2 of RR a holding circuit for the relay is established from ground, right-hand normal con- 130.

5 tact of PT, alternate contact of PON, alternate contact of 2 and winding of RR, negative battery, to ground, which holds the relay in its energized position so long as the 5 alternate contact of PON remains closed.

10 The energization of the relay RR' interrupts, by the opening of its normal contact 4, the traced circuit through the interrupter 1', and interrupts, by the opening of its 15 normal contact 1, the described initial holding circuit of the relay 509, whereupon the relay 509 is held in its energized position over a circuit from ground, winding of resistance coil 507, alternate contact 2 of 508, 20 alternate contact 2 and left-hand winding of 509, negative battery, to ground. The energization of relay RR', by the opening of its normal contact 2 also removes ground from the contact 501 which has been previously described as being placed at that point to prevent the selection of the minor group of connecting circuits by any other connecting circuit selector or secondary connecting circuit selector. The closure of alternate 25 contact 1 of RR' connects ground with the contact 418 of the allotter to prevent the brushes W^e and W^w coming to rest in connection with the passive contact terminals of the linked line finder and the connecting 30 circuit selector so long as the relay RR' remains energized. The closure of the alternate contact 2 of the relay RR' establishes a holding circuit for the relay from ground, left-hand normal contact of relay PT⁷, alternate 35 contact of PON', alternate contact 2 and winding of RR', negative battery to ground, which maintains the relay energized so long as the alternate contact of PON' remains closed.

40 Reverting to the described initial energization of relay 748, by the closure of its alternate contact 2 a holding circuit therefor is established from ground, contact 712 (closed at all positions of the brushes W¹⁸ except normal), alternate contact 2 and winding of 45 748, negative battery to ground, which maintains the relay in its energized position so long as the brushes W¹⁸ remain in an off-normal position. Also, by the closure of its alternate contact 4, connects ground through normal contact 2 of 747, contact 4 of 748, normal contact 1 of 708, normal contact 1 of 705, to the passive contacts 503 and 603 of each of the connecting 50 circuit selectors and secondary connecting circuit selectors, to the passive contacts of which the selective terminals of the connecting circuit are connected, to prevent the selection of the connecting circuit by any 55 such connecting circuit selector or secondary connecting circuit selector.

60 Simultaneously with the establishment of the holding circuit of the relay 752, circuits are established to cause the initial energization of relay 754 and the illumination of 65

lamp 701, which may be traced from ground, contact of 707, normal contact 4 of 706, contact 713 in multiple with contact 2 of 752, normal contact 4 of 750, normal contact 4 of relay RR³, normal contact 4 of 705, winding of relay 754, negative battery, to ground, and in multiple therewith through lamp 701, negative battery, to ground, which causes the illumination of lamp 701, which visually indicates to the operator the presence of a call on the associated connecting circuit.

70 The energization of relay 754 establishes a circuit from ground, left-hand normal contact 733, alternate contact 2 of 754, lower winding of 755, negative battery, to ground, which energizes the relay 755, connects the operator's telephone 762, with the line of the calling substation, through the contacts 2 and 3 thereof, to the talking strands of 85 the connecting circuit and line of the calling substation, as indicated by the heavily drawn lines, which enables the operator to converse with the calling subscriber and ascertain the number of the substation with which connection is desired. The closure of contact 1 of relay 754 establishes a circuit from ground, right-hand normal contact of 733, alternate contact 1 of 754, brush W¹⁸, its engaged contact 710, the corresponding lamp 90 734, negative battery, to ground, which causes illumination of the lamp 734 to indicate to the operator the class of the calling substation. In addition, the energization of relay 754, by the closure of its alternate contact 3, establishes circuit for the flow of current through the winding of the relay GBC' of the corresponding connecting circuit finder group, which responds, and, by 95 the interruption of its normal contact, disconnects ground from the corresponding group test contacts 801 of the connecting circuit finders (Fig. 8), which renders the group selectable by such finder switches.

100 By the closure of the alternate contacts 1 and 2 of the relay GBC', ground is multiply connected to the group test contacts 501 of each of the minor groups of the secondary group of connecting circuits, and, likewise, to the passive contacts 601 of each of the secondary connecting circuit selectors (Fig. 6), to the passive contacts of which are connected the connecting circuits of the secondary group, which renders them unselectable by the connecting circuit selectors, and secondary circuit 115 selectors seeking selection of idle connecting circuits.

Operation of connecting circuit finder.

120 The energization of relay GBC' establishes a circuit for the flow of current through the winding of relay PT¹⁴, from ground, alternate contact 3 of GBC', normal contact 1 of relay T', brush W²⁴, its engaged contact 806 corresponding to the allot-

ted connecting circuit finder then in normal position and with which is connected an impulse transmitter also in normal position, contact 3 of PON¹⁴, winding of relay PT¹⁴, 5 negative battery, to ground, which responds and establishes a vibratory circuit from ground, upper alternate contact of PT¹⁴, interrupter contact and winding of PM¹⁴, negative battery, to ground, by which the magnet PM¹⁴ is energized, and the brushes W¹⁹, to W²³ inclusive are moved one step in their primary selecting operation, during which movement, by the opening of normal contact 3 of PON¹⁴, the traced energizing 10 circuit of relay PT¹⁴ is interrupted, and, if the connecting circuit of the energized relay 754 be included in the first connecting circuit finder group, the relay PT¹⁴ will be deenergized. If, however, as is assumed, the 15 connecting circuit be in some other connecting circuit finder group, then, prior to the opening of contact 3 of PON¹⁴, a holding circuit will be established from ground, normal contact 3 of relay GBO' of the connecting circuit finder group multiply connected to the passive contacts 802 to 805 inclusive of the first row of the connecting circuit finders, first contact 801, brush W¹⁹ in connection therewith, lower alternate contact 20 and winding of PT¹⁴, negative battery, to ground, which will maintain the relay PT¹⁴ energized, continuing thereby the vibratory circuit through the winding of the magnet PM¹⁴, which will continue to be energized 25 and deenergized and the brushes W¹⁹ to W²³ inclusive moved step by step in their primary selecting operation, until the brush W¹⁹ engages a contact 801 multiply connected with the normal contact 3 of relay 30 GBC' of the connecting circuit finder group, in which is included the connecting circuit of the energized relay 754, when the traced holding circuit of the relay PT¹⁴ will be interrupted, owing to the interruption of the 35 normal contact 3 of the relay GBC', the relay PT¹⁴ deenergized, its alternate contacts opened, interrupting the traced vibratory circuit through the motormagnet PM¹⁴, preventing further rotation of the brushes in 40 their primary selecting operation.

The closure of the normal contact of PT¹⁴ establishes a circuit for the flow of current from ground, normal contact of PT¹⁴, alternate contact 2 of PON¹⁴, normal contact of 45 SON¹⁴, winding of ST¹⁴, negative battery, to ground, which energizes the relay ST¹⁴, whereupon by the closure of its alternate contact 2 a vibratory circuit for the motormagnet SM¹⁴ is established from ground, 50 alternate contact 2 of ST¹⁴, interrupter contact and winding of SM¹⁴, negative battery, to ground, which responds and rotates the brushes W²⁰ to W²³ inclusive one step in their secondary selecting operation into engagement with their first set of contacts 802

to 805 inclusive, terminals of the first connecting circuit of the selected connecting circuit finder group; whereupon, by the opening of the normal contact of SON¹⁴, the traced energizing circuit relay ST¹⁴ is interrupted, and, if the relay 754 of such connecting circuit be energized, the alternate contacts of relay ST¹⁴ will be interrupted, which will interrupt the traced energizing circuit through the magnet SM¹⁴ and cause 75 the selection thereby of the first connecting circuit of the connecting circuit finder group.

It is assumed, however, that the connecting circuit sought is some other than the first. Therefore, prior to the opening of normal contact of SON¹⁴ by the engagement of brush W²¹ with first contact 803, a holding circuit for the relay ST¹⁴ is established from ground, normal contact 3 of relay 754 of such connecting circuit, multiply connected passive contact 803, brush W²¹ now in connection therewith, alternate contact 3 of ST¹⁴, normal contact 2 of RR¹⁴, winding of ST¹⁴, negative battery, to ground, which holds the relay ST¹⁴ energized, maintaining the traced vibratory circuit through motormagnet SM¹⁴, resulting in the brushes W²⁰ to W²³ being rotated step by step into and out of connection with their associated passive contacts 802 to 805 inclusive of the selected row or group, until brush W²¹ engages the contact 803 connected with the normal contact 3 of the energized relay 754, when the relay ST¹⁴, owing to the interruption of normal 100 contact 3 of the relay 754, will be deenergized, and by the opening of its alternate contacts, interrupt its traced holding circuit and the traced vibratory circuit through the motormagnet SM¹⁴, leaving thereby the 105 brushes W²⁰ to W²³ inclusive in connection with their contacts 802 to 805 inclusive, the terminals of the connecting circuit sought.

Responsive to the deenergization of relay 110 ST¹⁴ and thereby the closure of its normal contact 3, a circuit for the flow of current is established from ground, normal contact 3 of ST¹⁴, brush W²¹ to the engaged multiply connected contacts 803 of the selected connecting circuit, which renders such connecting circuit unselectable by any other of the associated connected circuit finders. Upon the movement of the brushes W²⁰ to W²³ inclusive to engagement with the first set of 115 contacts 802 to 805 inclusive, respectively, a circuit, which causes the energization of relay 810, is established from ground, normal contact of relay PT¹⁴, alternate contact 2 of PON¹⁴, alternate contact of SON¹⁴, normal contact 1 of relay RR¹⁴, normal contact of relay 811, winding of relay 810, negative battery, to ground.

Following the deenergization of relay 120 ST¹⁴, the initial energization of relay RR¹⁴ 125

130

is effected by means of a circuit which includes ground, alternate contact 2 of relay ST¹⁴, alternate contact 2 of relay 810, winding of relay RR¹⁴, and negative battery, to ground, following which a holding circuit therefor is established, from ground, normal contact of PT¹⁴, alternate contact 3 and winding of RR¹⁴; negative battery, to ground. By the opening of normal contact 1 of relay RR¹⁴, the initial energizing circuit of relay 810 is interrupted and in lieu thereof a holding circuit therefor is established, which may be traced from ground, negative battery, winding of 810, contact 1 of 811, alternate contact 1 of RR¹⁴, normal contact 1 of ST¹⁴, brush W²⁰, its engaged passive contact 802, thence through winding of relay 756, normal contact 4 of 750, alternate contact 2 of 752, and in multiple therewith, contact 713, alternate contact of 751, normal contact 4 of 706 and contact of 707 to ground; whereby the relay 810 is maintained in its energized position and the relay 756 actuated, establishing a vibratory circuit from ground, interrupter I³, alternate contact 1 of 756, normal contact 1 of 757, normal contact 3 of 758, lamp 703, negative battery, to ground, causing the lamp 703 to flash in a distinctive manner, indicating to the operator, during such flashing, the connection with the associated connecting circuit of a connecting circuit finder and associated impulse transmitter.

Operation of impulse transmitters.

The call signal lamp 701 and class of service indicating lamp 734 being illuminated as described, and the operator's telephone in connection with the line of the calling substation, the operator challenges the calling subscriber to ascertain the number of the substation with which connection is desired.

As the description now proceeding is that of an intra-office connection, the line of the called substation will therefore terminate in the same office as the line of the calling substation. It is assumed that the office is designated "K" and that the numerical designation of the substation described is 5346. The operator, upon ascertaining the number of the called substation, will actuate from normal the eleventh, fifth, third, fourth and sixth key of the office, thousands, hundreds, tens and units group respectively of the recording keys of the position, whereupon a vibratory circuit through the windings of motormagnets MM³ of each section of the impulse transmitter (assuming the brushes of the connecting circuit finder to have reached connection with the terminals of the connecting circuit) is established, which include the master contacts 923 of the units and office keys, contact 4 of T³, brush W²⁷, its engaged passive contact 809, thence in multiple through contacts 913, interrupter

contact and winding of the motormagnet MM³ of each section, negative battery, to ground. The magnets MM³ are thereby actuated, each rotating its associated brush W²⁰ one step from connection with its first or normal passive contact to connection with its second passive contact 911, in the manner described in connection with Figs. 22 to 33 inclusive, resulting thereby in the interruption, by the opening of the contacts 913, of the respective sections of the initial energizing circuit for the magnets MM³, but the contacts 912 being now closed, the vibratory circuit for the magnets MM³ of each section is maintained, traceable from ground, its contact 912, right-hand outer normal contact of relay 924, interrupter contact and winding of the magnet MM³, negative battery, to ground; whereby the magnets continue to vibrate and move their associated brushes W²⁰ into and out of engagement with their associated passive contacts 911, multiply connected with the contacts of the recording keys of the corresponding group, until the brush W²⁰ engages its contact 911 connected with the actuated key of the associated group, which will be the twenty-second, third, fourteenth, eighth, ninth and thirteenth contact from normal of the district, office, thousands, hundreds, tens and units sections respectively, when a circuit for the associated relay 924 is established from ground, the key actuated, engaged contact 911, brush W²⁰, right inner normal contact and winding of the relay 924, negative battery, to ground, which actuates the relay and, by the opening of its outer right-hand normal contact, interrupts the traced vibratory circuit through contact 912 of the motormagnet MM³, preventing further rotation in its setting operation of the brush W²⁰.

Responsive to the movement of the brush W²⁰ of each section of the impulse transmitter from normal, by the opening of the contacts 916, the existing short circuit is removed from around the lower winding of relay 812, which is thereupon energized over a circuit for the flow of current from ground, alternate contact 4 of RR¹⁴, alternate contact 3 of 810, lower winding of 812, winding of resistance coil 816, negative battery, to ground, establishing circuit for the flow of current from ground, positive battery, winding of coil 961, contact 973 (when the brush of units section is in positions from 2 to 6 inclusive), or from ground, winding of relay 813 contact 922 (when the brush of units section is in positions from 6 to 18 inclusive), contact 4 of 812, brush W²⁰, its engaged contact 805, normal contact 3 of 757, left-hand normal contact of PON³, upper winding of relay RR³, negative battery, to ground, which energizes the relays 813 and RR³.

Responsive to the energization of relay 130

RR³, by the opening of its normal contact 4 the traced circuit for the flow of current through lamp 701, and through the winding of relay 754, is interrupted, the lamp extinguished and the relay deenergized, which 5 interrupts circuit for the flow of current through the connected indicator lamp 734, which is extinguished. The opening of alternate contact 2 of 754 interrupts the 10 traced circuit for the flow of current through the winding of relay 755, which is deenergized, and, by the opening of its contacts 2 and 3, disconnects the operator's telephone 15 762 from the talking strands of the connecting circuit and the calling substation. The opening of the alternate contact 3 of 754 20 interrupts the circuit through the winding of relay GBC', which returns to normal, and, by the opening of its contacts 1 and 2, disconnects ground from the group test contacts 501 and 601 of the connecting circuit 25 selectors and secondary connecting circuit 30 selectors. The opening of the alternate and closure of normal contact 3 of GBC' 35 rupts the starting circuit for the connecting circuit finders, and connects ground with the passive contacts 801 of the connecting circuit finders to prevent the selection of the corresponding connecting circuit finder 40 group.

The closure of alternate contact 4 of relay RR³ establishes a circuit from ground, negative battery, lower winding and alternate contact 4 of RR³, normal contact 4 of 750, 45 thence through alternate contact 2 of 752 and, in multiple therewith, through contact 713 and alternate contact of 751, through contact 4 of 706, and contact of 707 to ground, which maintains the relay RR³ in 50 its energized position.

Upon the energization of the relays 924 of each and all sections of the impulse transmitter, a short circuit then existing about the right-hand winding of the relay 814 is 55 removed and the relay energized over a circuit from ground, right-hand winding of relay 814, left-hand alternate contacts of each of the relays 924, winding of coil 818, negative battery, to ground, establishing a 60 circuit from ground, negative battery, winding of 818, alternate contacts of relays 924, returning over the previously traced path through the right-hand winding of 814 to ground, which maintains relay 814 energized during the energization of any of the 65 relays 924.

The closure of contact 2 of relay 814 establishes the initial energizing circuit for the relay 811 from ground, contact 2 of 814, 70 left-hand winding of 811, negative battery, to ground. The closure of the contacts of 814 establishes a circuit from ground, contact 3 of 814, passive contact 808, brush W²⁶ in engagement therewith, normal contact 3 of T', and thence in multiple through

contacts 923, winding of restoring magnets 906, of each group of recording keys, negative battery, to ground. The magnets 906 responding, restore, in any well-known manner, the actuated ones of the recording 70 keys. The energization of relay 811 establishes a circuit for the flow of current from ground, normal contact of PT¹⁴, alternate contact 2 of PON¹⁴, contact 4 and right-hand winding of 811, negative battery to 75 ground, which holds relay 811 in its energized position so long as the alternate contacts of PON¹⁴ remain closed. The closure of contact 3 of 811 establishes a circuit for the flow of current, from ground, contact 3 80 of 811, passive contact 807, brush W²⁶, winding of relay T', negative battery, to ground, which causes the energization of relay T', and by the closure of its contact 2, a vibratory circuit is established from ground, contact 2 of T', interrupter contact and winding of MM', negative battery, to ground, causing the brushes W²⁴ to W²⁷ inclusive 85 to be moved out of connection with their then engaged passive contacts into engagement with the passive contacts associated with the next succeeding idle connecting circuit finder and associated idle impulse transmitter. 90

The closure of alternate contact 3 of relay 95 T' connects ground with the restoring magnets 906 of the recording keys to prevent their being locked in their off-normal position during the movement of the brushes W²⁴ to W²⁷ in search of the passive contacts of an idle connecting circuit finder and associated impulse transmitter then idle. Upon the brush W²⁵ engaging a contact 807 connected with an idle connecting circuit 100 finder, as evidenced by the interruption of contact 3 of its associated relay 811, the circuit for the flow of current through the relay T' is interrupted, the relay deenergized, which, by the opening of its contact 2, interrupts the traced circuit through the 110 motormagnet MM², preventing further rotation of the brushes of the allotter. The closure of contact 1 of T' connects brush W²⁴ with the common starting conductor leading to the alternate contact 3 of the 115 relays GBC', whereby, upon the selection of an associated connecting circuit by a connecting circuit selector or a secondary connecting circuit selector, the starting circuit for a connecting circuit finder may be established. 120

By the closure of contact 4 of relay 814, as described, a circuit from ground, contact 4 of 814, contact of 813, contact 1 of relay 924, normal contact and winding of magnet RM³ 125 of the office section of the impulse transmitter, negative battery, to ground, is established, which results in the energization of the magnet RM³ and, in response thereto, the removal of the retaining pawl from the 130

- retaining ratchet wheel of the shaft of the office section of the impulse transmitter, allowing the brush $W^{20'}$ to return, in the manner described, to normal position, and thereafter sequentially establishes over the previously traced path and through contacts 918 (of each section of the impulse transmitter, except the units section) the initial energizing circuit through contact 1 of 924 of the respective sections, for the magnets RM^3 of each section. The sequential energization of the restoring magnets RM^3 establishes sequentially energizing circuits for the relay 815 traceable from ground, contact 2 of magnets RM^3 , contacts 914, winding of relay 815, negative battery to ground.

During the energization of relay 815, winding of relay 813 is, by the closure of the right-hand contact of relay 815, short circuited, which acts to hold the relay 813 deenergized; also, during the energization of relay 815 by the closure of its left-hand contact, ground is connected to the impulse contacts 915 of each section of the impulse transmitter. Upon the closure of alternate contact 1 of the magnets RM^3 , a maintaining circuit is established therefor, from ground, contact 912, alternate contact 1 and winding of RM^3 , negative battery to ground, which holds it in its energized position so long as the associated brush $W^{20'}$ remains in off-normal position.

Operation of district selectors.

- The brushes of the impulse transmitter having been adjusted to positions corresponding to the keys actuated, which, in turn, correspond to the number of the called substation and the restoring magnet RM^3 of the district section actuated, the brush $W^{20'}$ of such section is started on its return to normal, the contact 915 making and breaking connection between each position, as described, transmitting an impulse of current for each closure of the contact 915, from ground, left-hand contact of 815, contact 915, winding of coil 817, negative battery, to ground, and in multiple therewith, through contact 3 of 812, brush $W^{22'}$, its engaged passive contact 804, alternate contact 2 of 756, normal contact 2 of 757, normal contact of SON^3 , normal contact 4 of PT^3 , winding of PM^3 , negative battery, to ground, causing, for each closure and interruption of the contact 915, the energization and deenergization of the magnet PM^3 , which moves the brushes W^{10} to W^{21} inclusive step by step from row to row of passive contacts 1001 to 1006 inclusive.
- The brush $W^{20'}$ of the district section of the impulse transmitter having been adjusted to its twenty-second contact 911 during its restoration, there will be seventeen closures and interruptions of the contact 915, resulting in seventeen energizations and deener-

gizations of the magnet PM^3 which will cause the brushes W^{10} to W^{21} inclusive to be rotated in their primary selecting operation to the position with the brushes W^{10} to W^{21} inclusive, opposite the seventeenth row of 70 passive contacts 1001 to 1003 inclusive, the multiple selective terminals of the first minor group of fifteen local incoming selectors, and the brushes W^{22} to W^{24} in connection with the seventeenth set of contacts 1004, 75 to 1006 inclusive respectively. Thereafter, responsive to the continued return to normal of the district section of the impulse transmitter, when its brush $W^{20'}$ passes its fifth contact 911 from normal, circuit of the relay 80 815 is, by the opening of contact 914, interrupted, which, by the opening of its left-hand alternate contact, disconnects ground from the contact 915 and by the opening of its right-hand alternate contact removes the 85 then existing short circuits from around the windings of relays 813 and PT^3 , traceable, for the relay 813, from ground, right-hand contact of 815 to the winding of said relay, the opposite end of which is connected with 90 ground, and for the relay PT^3 , from ground, right-hand alternate contact of 815, contact 922 (now closed), contact 4 of 812, brush $W^{22'}$, its engaged passive contact 805, normal contact 3 of 757, alternate contact of 95 PON^3 , normal contact 1 of PT^3 , normal contact 1 of SON^3 to winding of PT^3 , the opposite end of which is connected with ground through right-hand alternate contact 2 of PON^3 ; whereupon the relays 813 and PT^3 100 are energized over a circuit traceable, for the relay PT^3 , from ground, right-hand alternate contact of PON^3 , winding of relay PT^3 , winding of resistance coil 1008, negative battery to ground, and for relay 813 from ground, winding of 813, contact 922 of the units section of the impulse transmitter, and thence over the previously traced path to and through winding of resistance 1008 in multiple with the winding of PT^3 to negative 110 battery, to ground.

Responsive to the energization of relay PT^3 , the traced circuit, through the relay 813, is, by the opening of normal contact 1 of PT^3 , interrupted, and is not again established until the brushes of the district selector are selectively brought into connection with an idle trunk line.

It has been stated that the number of trunk lines terminating in local incoming selectors multiply connected to a particular district selector are divided into three minor groups of fifteen each. It will now be assumed that there is an idle trunk in the first minor group, that is, the seventeenth row; 120 therefore, the group contact 1004 of the seventeenth row, now in connection with brush W^{22} , is connected with ground through the normal contact of the corresponding relay GBC^2 (Fig. 11), and the corresponding 125 130

contact 1005, in connection with brush W^{23} , which is connected with the alternate contact of GBC^2 , is disconnected from ground, with the result that following the energization of 5 relay PT^3 , as described, a circuit for the relay ST^3 is established, which may be traced from ground, normal contact of relay GBC^2 , passive contact 1004, brush W^{22} , contact 10 3 of SON^3 , alternate contact 2 of PT^3 , winding of ST^3 , negative battery, to ground, which energizes the relay ST^3 .
 The closure of alternate contact 2 of relay ST^3 establishes a vibratory circuit for the motor magnet SM^3 , from ground, contact 2 15 of ST^3 , interrupter contact and winding of SM^3 , negative battery, to ground, which responding, rotates the brushes W^{19} to W^{21} , inclusive, into connection with the first set of their associated set of passive contacts 20 1001 to 1003 inclusive. During such movement of the brushes, by the opening of contact 3 of SON^3 , the traced energizing circuit of ST^3 is interrupted, whereupon, if the trunk line of the engaged first set of contacts 25 1001 to 1003 be idle, the relay ST^3 will be de-energized, the traced circuit through SM^3 interrupted, and the brushes W^{19} to W^{21} left in connection with their respective contacts 30 1001 to 1003 inclusive, multiple terminals of such trunk line.

If, however, the trunk line multiply connected to the set of contacts 1001 to 1003 first engaged by the brushes W^{19} to W^{21} , respectively, be busy, the contact 1003 will be 35 connected with ground through the normal contact 4 of the relay ST^3 of some other district selector whereby, upon the engagement of brush W^{21} prior to opening of contact 3, of SON^3 with such contact 1003, a 40 maintaining circuit for the relay ST^3 will be established which may be traced from the ground, normal contact 4 of relay ST^3 , brush W^{21} , contact 1003 of the district selector then in selective connection with the 45 trunk, to contact 1003, brush W^{21} now engaging said contact, alternate contact 4 of ST^3 , alternate contact 1 of RR^3 , winding of relay ST^3 , negative battery, to ground; and as the brush W^{21} , during its rotation, engages the next succeeding contact 1003 before connection with the previous contact 50 1003 is interrupted, circuit for the relay ST^3 will be maintained, the relay held energized, the vibratory circuit through magnet SM^3 maintained, and the rotation of brushes W^{19} to W^{21} continued step by step, until the brush W^{21} engages a contact 1003 associated with and leading to a local incoming selector then idle, when circuit for the relay ST^3 55 is interrupted, owing to the absence of ground connection with the contact 1003, the relay de-energized, which, by the opening of contact 2 of ST^3 , interrupts circuit through SM^3 , preventing further rotation of the 60 brushes, whereby such trunk line is selected 65

and, by the closure of contacts 1 and 3 of ST^3 , the connecting circuit and the impulse transmitter connected therewith is extended to connection with the local incoming selector of such selected trunk line. 70

The return to normal of the relay ST^3 connects the passive contact 1003 of the selected trunk line with ground, which may be traced from ground, in multiple through normal contact 3 of 759 and normal contact 75 2 of 760, normal contact 4 of 709, normal contact 4 of ST^3 , brush W^{21} to the contact 1003, which is maintained so long as ST^3 remains de-energized, and prevents the selection by any other district selector of such 80 trunk line.

Following the first step of the brushes W^{19} to W^{21} , inclusive, in their secondary operation by the opening of the normal contacts of SON^3 , the magnet PM^3 is disconnected and rendered ineffective so long as the brushes of the district selector remain in an off-normal position. 85

Under the assumption that all of the trunk lines of the first minor group, in juxtaposition with which the brushes are brought in response to the impulses of current through the winding of the motormagnet PM^3 from the district section of the impulse transmitter, be busy, then the relay GBC^2 of such minor group will be energized, its normal contact opened and its alternate contact closed, with the result that the previously traced initial energizing circuit for the relay ST^3 will not be completed, but instead, owing to the connection of ground via the alternate contact of relay GBC^2 with the corresponding passive contact 1005, a vibratory circuit is established, following the removal of the traced short circuit from around the winding of relay PT^3 and its energization, for the magnet PM^3 , from ground, alternate contact of GBC^2 , contact 1005, brush W^{23} in engagement therewith, contact 3 of PT^3 , upper interrupter contact 10 of PM^3 , alternate contact 4 of PT^3 , winding of PM^3 , negative battery to ground, which responds and rotates the brushes W^{19} to W^{24} , inclusive, to the next succeeding row 110 of passive contact terminals of trunk lines of the second minor group of the group leading to the local incoming selectors, whereupon, if there be an idle trunk line connected to the passive contacts of such row, the traced vibratory circuit through 115 the motormagnet PM^3 is, owing to the de-energization of the associated relay GBC^2 , interrupted and the previously traced energizing circuit through the relay ST^3 , which includes the normal contact of the corresponding relay GBC^2 , established, which establishes the described circuit for the flow of current through the winding of magnet SM^3 , whereby the brushes W^{19} to W^{21} , inclusive, are rotated as described to connection 120 125 130

with the first encountered idle one of the trunk lines of the minor group; but, assuming all the trunks connected to the passive contacts of the second minor group to be 5 busy, the traced vibratory circuit through the motormagnet PM^3 is maintained and the brushes rotated beyond the second minor group to the third minor group, which, in the herein described arrangement, is the last 10 minor group of the directly selected group, and as the last minor group of a group does not contain a relay GBC^2 , the traced vibratory circuit through the motormagnet PM^3 is interrupted, and as the contact 1004 of the last minor group of each 15 group is connected with ground, the previously traced circuit through the relay ST^3 is established, followed by the establishment of the previously traced circuit through 20 SM^3 , whereupon the brushes W^{10} to W^{21} , inclusive, are rotated step by step into and out of engagement with their associated passive contacts of the selected minor group until a set multiply connected with the first 25 idle trunk line leading to and terminating in a local incoming selector are engaged, when the maintaining circuit through ST^3 is, in the manner described, interrupted, the relay ST^3 returned to normal, interrupting 30 thereby circuit for the flow of current through the winding of SM^3 , preventing further rotation of the brushes in their secondary selecting operation, and causing the extension, by the closure of contacts 1 and 35 3 of ST^3 , of the connecting circuit and the impulse transmitter connected therewith to connection with such selected local incoming selector.

The closure of normal contact 4 of ST^3 40 connects, as described, ground with the multiply connected test contact 1003 of the selected trunk.

Should all of the trunk lines connected with the passive contacts of the last row or minor 45 group of a selected group be busy, then the brushes would be rotated one step beyond the last set of contacts 1001 to 1003 inclusive, whereupon, owing to the disconnection of ground from the brush W^{21} , the relay ST^3 50 is deenergized, interrupting the vibratory circuit through winding of SM^3 , preventing further rotation of the brushes, in which position, by the closure of contacts of SOR^3 , the interrupter I^4 is connected with the lower 55 talking strand of the connecting circuit, and thence over the previously traced path through the winding of relay 813, which responding, connects ground over the previously traced path with the contacts 918 to 60 bring about, successively, the energization of magnets RM^3 to cause the restoration to normal of the remaining sections of the impulse transmitters, and thereafter upon the energization of relay 757, which is accom-

plished in the manner hereinafter described, 65 the interrupter I^4 is brought into series connection with relay 746 which responds, causing the energization of relay 758, and thereafter, for each closure of the brushes of interrupter I^4 with its live segments, the relay 70 746 is caused to be energized followed by its deenergization; whereby the lamp 704 is caused to flash and indicate to the operator that all available paths leading to the final 75 selectors, to the passive contacts of which are multiply connected the called terminals of the line of the desired substation, are in use, and that the connection cannot be then established; whereupon the operator, after 80 advising the calling subscriber of the condition, will effect the restoration of the apparatus in the manner to be hereinafter described.

Operation of local incoming selectors. 85

Following the selection of an idle local incoming selector, circuit for the flow of current is established through the windings of relay 813, and the relay RR^4 of the local incoming selector, which may be traced from 90 ground, winding of 813, contact 922 (now closed) of the units section of the impulse transmitter, contact 4 of 812, brush W^{21} , engaged, contact 805, normal contact 3 of 95 757, contact 3 of ST^3 , brush W^{20} , its engaged contact 1002, a multiple terminal of the selected trunk line, normal contact 2 of PON^4 , lower winding of relay RR^4 , negative battery to ground, energizing the relays 813 and RR^4 , which, in respect to relay RR^4 , by the 100 closure of its contacts 1 and 3, establishes circuits for the flow of current through the windings of the differentially wound relay 1108 and the upper winding of RR^4 from ground, negative battery, thence in multiple 105 through the lower winding of 1108, upper winding and contact 3 of RR^4 , passive contact 1003, brush W^{21} , normal contact 4 of ST^3 , thence over the previously traced path 110 through normal contact 3 of 759, and in multiple therewith, through normal contact 2 of 760 to ground, which maintains the relay RR^4 in its energized position so long as the normal contact 4 of ST^3 remains closed, and for the upper winding of 1108 from 115 ground, contact 1 of RR^4 , upper winding of 1108, negative battery to ground. Owing to the differential arrangement of its windings, the relay 1108 is not actuated, but, upon the actuation from normal of the key 120 709 by the interruption of its normal contact 4, or the simultaneous energization of relays 759 and 760, direct ground is disconnected, which removes the short circuit from around the winding of coil 1009, 125 which reduces the flow of current through the lower winding of 1108 sufficiently to allow the attraction of its armature to cause,

in the manner to be hereinafter described, the connection of signaling currents with the lines of called substations.

The energization of relay 813, responsive to the circuit last traced, upon the return to normal of the district section of the impulse transmitter, establishes circuit for the flow of current over the previously traced path to the contact 918 of the district section of the impulse transmitter; thence through contact 1 of 924, normal contact 1 and winding of RM³ of the office section of the impulse transmitter, which energizes the magnet RM³, whereby the brush W²⁹ of the office section is, in the manner described, restored to normal, but, owing to the fact that the brush W²⁹ of the office section is adjusted to connection with its third contact, the contact 915 will not be closed. The section will, therefore, be restored to normal without the transmission of impulses to the local incoming selector.

Immediately following the return to normal of the office section of the impulse transmitter, the initial energizing circuit of the restoring magnet RM³ is established over the previously traced path to the contact 918 of the office section, and thence through contact 1 of 924, normal contact 1 and winding of RM³ of the thousands section of the impulse transmitter, negative battery, to ground, whereby the brush W²⁹ of the thousands section of the impulse transmitter is started on its return to normal, and a circuit for the flow of current established from ground, contact 2 of RM³, contact 914 (now closed) of the thousands section of the impulse transmitter, winding of 815, negative battery, to ground, which energizes the relay 815, and, by the closure of its contacts, short-circuits the winding of 813, and, upon the first step of the brushes W²⁹ to W³⁰, inclusive, of the local incoming selector, short-circuits the winding of relay PT⁴ over the previously traced path to contact 3 of ST³, and thence through brush W²⁹, its engaged contact 1002, alternate contact 2 of PON⁴, contact 1 of PT⁴, normal contact 1 of SON⁴ to one terminal of the winding of PT⁴, the other terminal of said winding leading to ground through contact 1 of PON⁴, which prevents the energization of relay PT⁴ during the energization of relay 815.

The closure of the left-hand contact of relay 815 connects ground to the contacts 915 of the impulse transmitter, resulting, during the return of the brush W²⁹ of the thousands section to normal, in the transmission of nine impulses of current through the motormagnet PM⁴ over the previously traced path to contact 1 of ST³, thence through brush W¹⁰, its engaged passive contact 1001, normal contact 3 of 1109, contact 2 of SON⁴, normal contact 4 of PT⁴, winding of PM⁴, negative battery, to

ground; causing thereby nine energizations and deenergizations of the magnet PM⁴, whereby the brushes W²⁹ to W³⁰ inclusive are moved into juxtaposition with their ninth row of passive contacts 1101 to 1103 inclusive, multiple terminals of hundreds selector switches of the first minor group of the fifth thousands group multiply connected to the passive contacts of a particular plurality of local incoming selectors, in which is included the local incoming selector being actuated. Following the transmission of the impulses through contact 915, when the brush W²⁹ of the thousands section reaches its fifth contact from normal, the circuit of the relay 815 is, by the opening of contact 914 of the thousands section of the impulse transmitter, interrupted, the relay 815 deenergized, its contacts interrupted, disconnecting ground from the contacts 915 and removing the then existing short-circuit, previously traced, from around the winding of the relay PT⁴ of the local incoming selector and the relay 813. The relay PT⁴, as a result of the removal of the short-circuit, is energized over a circuit from ground, alternate contact 1 of PON⁴, winding of relay PT⁴, winding of resistance 1110, negative battery to ground, whereby the previously traced circuit which included contact 4 of PT⁴ through the magnet PM⁴, is interrupted, and, by the closure of contacts 3 and 4 of PT⁴, the magnet PM⁴ is connected with the brush W²⁹, with the result that should all of the trunks of the first minor group, before which the brushes are then positioned, responsive to the described energizations of magnet PM⁴, be busy, the contact 1105, then engaged by the brush W²⁹, will be connected with ground through the alternate contact of relay GBC⁶ of the minor group, which is energized during the simultaneous busy condition of all trunks of the associated minor group, a vibratory circuit is established for the motormagnet PM⁴, which may be traced from ground, alternate contact of GBC⁶, multiply connected with 1105, brush W²⁹ now in engagement with the contact 1105, contact 3 of PT⁴, upper interrupter contact of PM⁴, alternate contact 4 of PT⁴, winding of magnet PM⁴, negative battery, to ground. The magnet PM⁴, responding, moves the brushes W²⁹ to W³⁰, inclusive, one step to the position corresponding to the second, and in the herein illustrated arrangement, the last minor group of the directly selected group; whereupon, owing to the absence of ground connection with the corresponding contact 1105, the traced vibratory circuit through the motormagnet PM⁴ is interrupted, and as the contact 1104, corresponding to the last minor group of each group of trunks terminating in passive contacts of the local incoming selectors, is in

permanent connection with ground, circuit is established for the relay ST^4 , which may be traced from grounded contact 1104, brush W^{28} now in engagement therewith, normal contact 3 of SON^4 , contact 2 of PT^4 , winding of ST^4 , negative battery to ground. The relay ST^4 responding, establishes a vibratory circuit from ground, contact 2 of ST^4 , interrupter contact and winding of SM^4 , negative battery to ground, for the magnet SM^4 , which responds and moves the brushes W^{25} to W^{27} , inclusive, one step in their secondary selecting operation, into connection with the multiply connected passive contact terminals of the first trunk line of the selected minor group.

During the movement of the brushes to connection with their first set of contacts of the selected minor group 1, by the closure of alternate contact 1 of SON^4 , the winding of relay PT^4 is short circuited and deenergized, and by the opening of normal contact 3 of SON^4 , the initial energizing circuit of relay ST^4 via brush W^{28} is interrupted, which, unless the trunk line connected with the first set of passive contacts 1101 to 1103, inclusive, be busy, will cause deenergization of the relay ST^4 and thereby by the interruption of circuit through winding of SM^4 .

Assuming, however, the trunk line connected with the first set of passive contacts of the minor group to be busy, its test contact 1103 is connected with ground; therefore a maintaining circuit for the relay ST^4 from grounded contact 1103, brush W^{27} , now in engagement therewith, alternate contact 4 of ST^4 , alternate contact 4 of RR^5 , winding of relay ST^4 , negative battery, to ground, is established and the relay maintained in its energized position, thereby maintaining the traced vibratory circuit through the winding of motormagnet SM^4 , which continues to be energized and deenergized, moving the brushes W^{25} to W^{27} , inclusive, into and out of engagement with their associated passive contacts 1101 to 1103, inclusive, multiple terminals of trunk lines leading to and terminating in the hundreds selectors of the selected minor group, until the brush W^{27} engages a test contact 1103 multiply connected with a trunk line then idle, when the described maintaining circuit through the relay ST^4 , owing to the absence of ground connection with the contact 1103, is interrupted, the relay ST^4 deenergized, which interrupts the traced vibratory circuit through the motormagnet SM^4 , preventing the further rotation of the brushes, whereby they are left in connection with their then engaged contacts 1101 to 1103 inclusive, multiple terminals of such trunk line. The closure of contacts 1 and 3 of ST^4 extends the connecting circuit and the impulse transmitter in connection therewith to a connection with the selected hundreds selector, and by the closure of normal contact 4 of ST^4 , ground is connected through the brush W^{27} to contact 1103, multiply connected with the test conductor of the selected hundreds selector, to prevent selection of such trunk line so long as brushes of the local incoming selector remain in connection with the trunk line.

Following the selection by the local incoming selector of an idle trunk line terminating in a hundreds selector, the relay 813 of the connecting circuit finder and the relay RR^5 of the hundreds selector are energized over the previously traced circuit to contact 3 of ST^4 , thence through brush W^{26} , its engaged contact 1102, normal contact of PON^5 , right-hand winding of RR^5 , negative battery, to ground.

The energization of relay RR^5 establishes a holding circuit, from ground, normal contact 4 of ST^4 , brush W^{27} , its engaged contact 1103, contact 2 and left-hand winding of RR^5 , negative battery, to ground, which holds the relay RR^5 in its energized position so long as the normal contact 4 of ST^4 remains closed.

Operation of hundreds selectors.

The energization of relay 813, as last described, upon the return to normal and the closure of contact 918 of the thousands section of the impulse transmitter, establishes the initial energizing circuit of magnet RM^3 of the hundreds section of the impulse transmitter over the previously traced path through contact 918 of the thousands section of the register, and thence through contact 1 of 924, normal contact and winding of RM^3 of the hundreds section of the impulse transmitter, negative battery, to ground, which responds and establishes a holding circuit from ground, contact 912, alternate contact 1 and winding of magnet RM^3 , negative battery, to ground, which holds the magnet RM^3 in its energized position so long as its brush W^{29} remains in an off-normal position.

As described, the energization of the magnet RM^3 allows its brush W^{29} to return to normal; also, by the closure of the contact 2 of RM^3 of the hundreds section, ground is connected with the now closed contact 914, which establishes an energizing circuit in the manner previously described for the relay 815, whereby, in the manner described, ground is connected with the contact 915 of the hundreds section of the impulse transmitter, the relay 813 short-circuited, and upon the movement of the brushes of the hundreds selector one step from normal in their primary selecting operation, the winding of relay PT^6 is short-circuited.

As the brush W^{29} of the hundreds section of the impulse transmitter was adjusted

to connection with its eighth contact from normal, during its return three impulses of current will be transmitted through its contact 915 over the previously traced path to contact 1 of ST⁴, thence through brush W²⁵, its engaged contact 1101, contact 2 of SON⁵, normal contact 4 of PT⁵, winding of PM⁵, negative battery, to ground, which energizes and deenergizes PM⁵, rotating the brushes W³¹ to W³⁵ inclusive three steps in their primary selecting operation, in juxtaposition with the multiply connected passive contacts of trunk lines of the first minor group of trunks leading to and terminating in final selectors, to the passive contacts of which are connected the called terminals of the third and fourth hundreds of the fifth thousand line group.

When the brush W²⁹ of the hundreds section of the impulse transmitter, after transmission of the impulses of current through the winding of motormagnet PM⁵, reaches its fifth contact from normal, the energizing circuit, by the opening of contact 914 of the relay 815, is interrupted; the relay deenergized, and, by the opening of its contacts, removes the short-circuit from around the winding of relay PT⁵ and the short-circuit from around the winding of relay 813, whereby relay PT⁵ is energized over a circuit from ground, right-hand contact of PON⁵, winding of relay PT⁵, winding of resistance coil 1206, negative battery to ground.

Responsive to the energization of relay PT⁵, by the opening of its normal contacts and the closure of its alternate contacts, the energizing circuit of the relay 813 is interrupted, the winding of magnet PM⁵ disconnected from the talking strand of the selected trunk lines and connecting circuit, and connected through alternate contacts 3 and 4 of PT⁵ with brush W³⁵, and connects the brush W³⁴ through contact 2 of PT⁵ with relay ST⁵.

Assuming that all trunk lines of the first minor group of the group selected, responsive to the impulses of current through the winding of magnet PM⁵, transmitted through the hundreds section of the impulse transmitter, be in use, the corresponding relay GBC⁶ will be energized, its normal contact interrupted and its alternate contact closed; then following the energization of relay PT⁵ a vibratory circuit is established through the winding of PM⁵, from ground, alternate contact of relay GBC⁶ (Fig. 13), passive contact 1205, brush W³⁵ now in engagement therewith, contact 3 of PT⁵, interrupter contact of PM⁵, alternate contact 4 of PT⁵, winding of magnet PM⁵, negative battery, to ground, which energizes the magnet PM⁵, causing the brushes of the hundreds selector to be moved one step beyond the first minor group to the next succeeding; and, in the

herein illustrated arrangement, the last minor group of the directly selected group, whereupon, owing to the absence of ground connection with the brush W²⁵, further actuation of the magnet PM⁵ is prevented, and as the contact 1204 of the last minor group of each group of trunk lines multiply connected with the passive contacts of the hundreds selector is permanently connected with ground, circuit is established from grounded contact 1204, brush W³⁴ in engagement therewith, contact 3 of SON⁵, contact 2 of PT⁵, winding of relay ST⁵, negative battery, to ground, which energizes the relay ST⁵ and establishes a vibratory circuit for the magnet SM⁵ which rotates the brushes W³¹ to W³⁵, inclusive, step by step into and out of connection with their associated passive contacts 1201 to 1203 inclusive, until the set of passive contacts, to which is connected a final selector then idle, are engaged, when circuit through the relay ST⁵ is interrupted, followed by the interruption of the vibratory circuit through magnet SM⁵, which prevents further movement of the brushes, and by the closure of contacts 1 and 3 of ST⁵, the selected final selector is connected with the talking strands of the connecting circuit, and therethrough with the impulse transmitter. The closure of normal contact 4 of ST⁵ connects ground through brush W³³ to the passive contact 1203 multiply connected with the test conductor of a selected final selector.

Operation of final selector.

Immediately following the selection of a final selector, circuit is established for the relays 813 and RR⁶, from ground, winding of relay 813 and thence over the previously traced path to contact 3 of ST⁵, brush W³², its engaged contact 1202, normal contact of PON⁵, right-hand winding of relay RR⁶, negative battery, to ground, which are energized, and in respect to relay RR⁶, by the closure of its alternate contact, a holding circuit therefor is established from ground, normal contact 4 of ST⁵, brush W³³, its engaged contact 1203, alternate contact 2 and left-hand winding of relay RR⁶, negative battery, to ground, which maintains the relay RR⁶ in its energized position so long as relay ST⁵ remains deenergized.

The energization of relay 813, as last stated, if the hundreds section of the impulse transmitter has returned to normal, establishes circuit for the flow of current over the previously traced path to the contact 918 of the hundreds section of the impulse transmitter, and thence through contact 1 of relay 924, normal contact 1 and winding of the restoring magnet RM³ of the tens section, negative battery, to ground, causing the energization of the restoring magnet RM³ of said tens section, where-

upon a holding circuit is established therefore through contact 912 of the section which holds the magnet in its energized position, whereupon, as described, its brush $W^{29'}$ 5 turns to normal.

The closure of contact 2 of RM^3 connects ground with contact 914, as described in connection with the other sections of the impulse transmitter, which brings about the 10 energization of relay 813 and, upon the first step of the brushes of the final selector from normal, by the closure of the lower alternate contact of PON^6 , places a short-circuit around the winding of PT^6 over the previously traced path to contact 3 of ST^6 , and thence through brush W^{32} , engaged passive contact 1202, lower alternate contact PON^6 , normal contact 4 of relay BFR, contact 4 of relay 1307, normal contact 4 of relay PT^6 15 to one terminal of the winding of PT^6 ; the other terminal being connected to ground through alternate contact 3 of RR^6 and upper contact of PON^6 .

The brush $W^{29'}$ of the tens section of the 25 impulse transmitter having been adjusted to connection with its eleventh contact from normal, during its return there will be four closures and interruptions of its contact 915, transmitting thereby over the previously traced path to contact 1 of ST^6 and thence through brush W^{31} , its engaged passive contact 1201, normal contact 3 of 1307, normal contact 3 of BFR, normal contact 1 of PT^6 , winding of PM^6 , negative battery, to 35 ground, four impulses of current which result in four energizations and deenergizations of the magnet PM^6 , which rotates the brushes W^{36} to W^{41} , inclusive, to the fourth row or minor group of passive contacts 1301 40 to 1304 inclusive, multiple called terminals of the fourth tens group of the second hundreds group of the lines of the fifth thousands group with which is connected the multiple called terminals of the line of the 45 substation being called.

Should the hundreds digit of a called substation be even, that is, 2, 4, 6, 8 or 0, then the relay 960 of the tens section of the impulse transmitter (Fig. 9, part 2) is 50 not energized until the closure of contact 920, which does not occur until after the brush $W^{29'}$ of the section disconnects, in its forward movement, from its fifteenth contact from normal. Thus, if the numerical 55 designation of a called substation be, as an example, 5446, the brush $W^{29'}$ will be adjusted to connection with the nineteenth contact 911 from normal instead of its ninth contact 911, as stated in the description of 60 the connection with the called substation 5346, the result being that the brushes of the final selector, in response to the impulses from the tens section, will be adjusted to the fourteenth row of passive contacts, terminals of the fourth tens groups, 65

of the fourth hundreds of the fifth thousands group of lines. The operation in the establishment of the connection would otherwise be as described in the establishment of connection with the line 5346.

By the continued rotation of brush $W^{29'}$ 70 of the tens section of the impulse transmitter to normal, after the transmission of the impulses, as stated, upon the disconnection of the brush from its fifth contact from normal, circuit for the relay 815, through contact 914 of the tens section of the impulse transmitter, is interrupted, the relay deenergized, and the mentioned short circuits removed from around the windings of 75 relays 815 and PT^6 ; whereupon the relay PT^6 is energized over a circuit for the flow of current from ground, upper contact of PON^6 , alternate contact 3 of RR^6 , winding of PT^6 , winding of coil 1310, negative battery, to ground, which disconnects the magnet PM^6 from the impulse transmitter, and establishes the initial energizing circuit for 80 the relay ST^6 from grounded passive group contact 1305, brush W^{40} , alternate contact 90 3 of PT^6 , upper normal contact 2 and winding of ST^6 , negative battery to ground, which responding, by the closure of its alternate contact 2, a holding circuit therefor is established from ground, upper contact of 95 PON^6 , alternate contact 3 of RR^6 , alternate contact 2 and winding of ST^6 , negative battery to ground, and simultaneously therewith, by the closure of contact 1 of ST^6 , the magnet SM^6 is connected to the 100 upper talking strand of the selected trunks, and thence through the connecting circuit to the impulse transmitter.

Immediately following the energization of ST^6 , relay 813 is energized over a circuit for 105 the flow of current, as previously traced, to the alternate contact of PON^6 , thence through normal contact 4 of BFR, contact 4 of 1307, contact 4 of ST^6 , winding of resistance coil 1312, negative battery, to 110 ground, and connects ground with the contact 918 of the tens section of the impulse transmitter, establishing thereby an energizing circuit for the restoring magnet RM^3 115 of the units section of the impulse transmitter over the previously traced path to contact 918 of the tens sections, thence through contact 1 of relay 924, normal contact 1 and winding of RM^3 of the units section, negative battery, to ground, whereupon, by the 120 closure of its alternate contact 1, a holding circuit traceable from ground, contact 912, alternate contact 1 and winding of PM^3 negative battery, to ground, is established, which holds the magnet in its energized position so long as the brush $W^{29'}$ of the section 125 remains in an off-normal position.

The closure of contact 2 of magnet RM^3 of the units section connects ground with the associated contact 914, which establishes 130

an energizing circuit for the relay 815, which is actuated, and, by the closure of its contacts, connects ground to the contact 915 of the units section and places a short-circuit, 5 in the manner described, around the winding of relay 813, which is deenergized.

The energization of magnet RM^a of the units section disconnects the retaining pawl 10 from the ratchet wheel of the shaft of the section, whereupon the brush returns to normal, during which, responsive to the closures and interruptions of contact 915 of the units section, six impulses of current are transmitted through the winding of motormagnet 15 SM^a, which may be traced from ground, alternate contact of 815, contact 915 of units section, thence over the previously traced path to normal contact 3 of 1307, contact 3 of BFR, contact 1 of ST^a, normal contact of 20 XT, winding of SM^a, negative battery, to ground, causing same to be energized and deenergized in response to each such impulse, whereby the brushes W^{2a} to W^{3a} inclusive are moved step by step to connection 25 with the sixth set of contacts 1301 to 1304 inclusive of the row.

Immediately following the transmission of the impulses last described, when the brush W^{2a} of the units section of the impulse transmitter is disconnected from its 30 seventh passive contact from normal, by the opening of its contact 914, the circuit through relay 815 is interrupted, the relay deenergized, its contacts opened, disconnecting ground from the contact 915 of the units section of the impulse transmitter, removing the described short-circuit from around the winding of relay 813 and the existing short-circuit from around the winding of 35 the slow release relay 1308, whereupon the relay 1308 is energized over a circuit for the flow of current from ground, contact of SON^a, normal contact 1 of BFR, normal contact 2 of 1307, winding of 1308, winding 40 of 1312, negative battery, to ground, establishing a circuit, whereby the relay 1309 is energized, its contacts closed, and the initial energizing circuit established for the relay 1307, which may be traced from ground, 45 normal contact 1 of BFR, contact 1 of 1309, winding of 1307, negative battery to ground.

The closure of contact 2 of 1309 connects ground with one terminal of the winding of the line test relay LTR, and in multiple 50 therewith places a short-circuit around the upper left-hand winding and lower winding of the relay XT.

The energization of relay 1307, by the opening of its normal and the closure of its 55 alternate contact 2, interrupts circuit through 1308, and establishes a holding circuit for the relay 1307, which includes normal contact 1 of BFR and contact of SON^a.

The energization of relays 1307 and 1309 60 connects brush W^{3a} to the upper talking

strand of the selected trunk, which may be traced through contact 3 of 1309 and alternate contact 3 of 1307.

The energization of relay 1307, by the closure of its contact 1, connects the brush W^{3a} with the left-hand terminal of the winding of the relay LTR, the right-hand terminal of which is, as described, now connected with ground through contact 2, of 70 1309, whereby the busy or idle condition of 75 the line of the called substation is ascertained.

If the line be an individual or multi-party line and busy, the relay LTR will not be actuated for the reason that the characteristics of the relays LTR are such that a second relay LTR will not be sufficiently energized to actuate its contacts when placed in multiple connection with another relay LTR or when multiply connected with a relay 510 80 (Fig. 5) or when in multiple connection with a coil 507 (Fig. 5); whereupon, following the deenergization of the relay 1309, responsive to the interruption of its circuit through contact of relay 1308 (upon its deenergization as the result of the interruption of its circuit by the opening of normal 85 contact 2 of relay 1307 at the time of its energization), the short-circuit around the upper left-hand winding and lower winding of relay XT is, by the opening of contact 2 of 1309, interrupted, the relay energized, its armature moved downward, which closes its alternate contact 2 and establishes a circuit from ground, alternate contact 2, 90 lower winding of BFR, negative battery, to ground, whereby the relay BFR is energized, its normal contact 1 opened, interrupting the holding circuit for the relay 1307, which returns to normal and, by 95 the closure of its alternate contact, a holding circuit is established which maintains the relay BFR energized so long as the contact of SON^a remains closed.

By the closure of the alternate contact 4 110 of relay BFR, interrupter I^a is connected to the lower talking strand of the selected trunks, and upon disconnection of the impulse transmitter from the connecting circuit, circuit is completed from ground, 115 interrupter I^a, thence over the common conductor to alternate contact 4 of BFR, lower alternate contact of PON, thence through the hundreds selector, local incoming selector, district selector, alternate contact 120 3 of 757, winding of relay 746, negative battery, to ground. The relay 746, upon its response to the first impulse from the interrupter I^a, by the closure of its alternate contact, establishes circuit for the 125 flow of current through the left-hand winding of relay 758, which is energized and, by the closure of its alternate contact 2, a holding circuit therefor is established, which may be traced from ground, contact 2 of 130

709, alternate contact 1 of 757, alternate contact 3 and right-hand winding of 758, negative battery, to ground. Thereafter, responsive to each interruption of the flow of current from interrupter I^2 through the winding of relay 746, circuit is established, from ground, normal contact of 746, contact 4 of 758, through lamp 704, negative battery, to ground, which causes the lamp 10 to flash for each impulse of current transmitted through the interrupter I^2 and visually indicate to the operator that the line of the called substation is, at the time, busy, and that the connection cannot be 15 established.

Assuming now the line of the substation called to be of the individual line (Fig. 1), private branch exchange (Fig. 2) or multi-party line (Fig. 3) class, and to be idle at 20 the time of its selection, then upon connection of the relay LTR with the brush W^{32} , responsive to the energization of relay 1307, as described, the relay LTR and the cut-off relay of the selected line will be energized 25 over a circuit for the flow of current, which may be traced from ground, contact 2 of 1309, winding of LTR, contact 1 of 1307, brush W^{32} , engaged passive contact 1303, thence over the multiply connected test conductor, if the line be an individual line, to 30 normal contact of line message register MR—if the line be so equipped—if not, over the dotted line bridging the normal contact of MR, winding of relay CO, negative battery, to ground; or if the line be of the 35 private branch exchange class, through the normal contact of message register MR^2 —if the line be so equipped—if not, over the dotted line bridging the normal contact of 40 MR^2 , winding of cut-off relay CO^2 , positive battery to ground; or, if the line be a multi-party line (Fig. 3), the circuit will extend from the test contact 1303, over the multiply connected test conductor, direct to and 45 through the winding of cut-off relay CO^2 , negative battery to ground.

The message registers MR and MR^2 , multiply connected with the relays CO and CO^2 respectively, are so adjusted as not to 50 be actuated when connected in series with relays LTR.

Responsive to the energization of relay LTR, the initial energizing circuit of the relay CR^6 is established from ground, contact 55 of SON^6 , normal contact 1 of BFR, contact 2 of LTR, winding of CR^6 , negative battery, to ground, which responds, and, by the closure of its contacts 1 and 2, connects the terminals of the line of the called substation 60 with the talking strands of the selected trunks and connecting circuit.

The energization of relay CR^6 by the closure of its contact 3, short circuits the winding of the lower coil and right-hand winding 65 of the upper coil of the relay XT, which

renders the selected line unselectable by any other of the final selectors, to the passive contacts of which are multiply connected its called terminals.

Assuming now the line selected to be the 70 first one of a plurality leading to and terminating at a substation of the private branch exchange class, and assuming the line to be, at the time, busy, then the relay LTR will not, for the reasons stated, be actuated, with 75 the result that, upon deenergization of the relay 1309 and the opening thereby of its contact 2, the short-circuit previously traced for the upper right-hand winding and lower winding of relay XT is removed, and said 80 windings placed in serial connection with the winding of relay LTR, with the result that the relay XT will be energized over the previously traced circuit for the relay LTR through the relay CO^2 to positive battery, 85 its armature moved upward, interrupting its normal and closing its alternate contact 1, establishing a vibratory circuit for the magnet SM^6 from ground, normal contact 1 of LTR, interrupter contact of SM^6 , contact 90 1 of XT, winding of SM^6 , negative battery, to ground. The magnet SM^6 responding thereto, automatically rotates the brushes W^{32} to W^{33} inclusive step by step into and out of connection with their corresponding 95 passive contacts, multiple terminals of lines of the private branch exchange class leading to and terminating at the same substation, until the test passive contact terminal 1303 of an idle one of such lines is engaged by the 100 associated brush W^{32} , whereupon the relay LTR is energized over a circuit for the flow of current from ground, winding of lower coil and winding of left-hand upper coil of XT, winding of LTR, contact 1 of 1307, 105 brush W^{32} , and thence through the cut-off relay CO^2 to positive battery, as previously described.

The energization of relay LTR at this time, by the opening of its normal contact 1, 110 interrupts the traced vibratory circuit through the motormagnet SM^6 , and, by the closure of its contact 2, establishes the previously traced energizing circuit for the relay CR^6 , which responds, connecting the 115 talking strands of the selected line to the connecting circuit, and short-circuits, in the manner described, the upper left-hand winding and lower winding of relay XT.

Assuming now that the line of the called 120 substation desired be of the private branch exchange class, that such lines do not exceed ten in number, and that all lines leading thereto be busy, then the brushes W^{32} to W^{33} inclusive are, in the manner described, rotated into and out of connection with all of the lines leading to the desired substation, to connection with the next adjacent set of passive contacts, terminals of the line of the individual class or multi-party class; where- 125 130

- upon the upper left-hand winding and lower winding of the coils of XT will be disconnected from positive battery and brought into connection, through the cut-off relay 5 CO, or CO^a of such line, with negative battery, thereby reversing the direction of the flow of current through the said windings of relay XT, with the result that the armature of the relay XT will be moved downwardly, 10 interrupting, by the opening of alternate contact 1 of XT, the traced vibratory circuit through the magnet SM^a, which will leave the brushes in connection with the passive contacts, multiple terminals of such line.
- 15 The downward movement of the armature of XT in addition, by the closure of its contact 2, establishes circuit for the flow of current through the winding of the relay BFR from ground, contact 2 of XT, lower winding of BFR, negative battery, to ground, which responding, by the closure of its alternate contact 1, establishes a holding circuit therefor, whereby the relay is maintained in its energized position as long as 20 contacts of SON^a remain closed.
- 25 The opening of normal contact 1 of BFR interrupts the described holding circuit of relay 1307, which returns to normal. The closure of alternate contact 4 of BFR establishes the previously traced circuit from the interrupter I^a through the winding of relay 30 746 to cause the flashing of the called supervisory lamp 704, in the manner described, to indicate to the operator the busy condition of the lines leading to the desired substation.
- 35 The deenergization of relay 1307, responsive to the interruption of its holding circuit through normal contact 1 of BFR, by the opening of its contact 1 disconnects the relay LTR and the relay XT from the test brush W²⁹, whereupon the relays XT and LTR (which would also, had the line been idle, be actuated) are restored to normal.
- 40 Assuming now the called substation to be of the private branch exchange class and the lines leading thereto greater in number than the sets of contacts of a row, the units digit of the number of the substation will be 1, and assuming that all the lines of the 45 directly selected row be busy, then during the continued rotation of the brush W²⁹ of the tens section of the impulse transmitter, after the transmission of the impulses 50 as stated, upon disconnection of the brush from its fifth contact from normal, circuit for the relay 815 through contact 914 of the tens section is interrupted, the relay de-energized and the mentioned short circuits 55 removed from around the windings of relay 818 and relay PT^a; whereupon the relay PT^a is energized over a circuit for the flow of current from ground, upper contact of PON^a, alternate contact 3 of RR^a, winding of PT^a, winding of coil 1310, negative 60 battery, to ground, which, by the closure of its contacts, establishes a vibratory circuit for the magnet PM^a from ground, alternate contact of the relay GBC, corresponding to the directly selected row and now energized, passive group contact 1306, now in engagement with brush W⁴¹, contact 2 of PT^a, upper interrupter contact of PM^a, normal contact 3 of ST^a, alternate contact 1 of PT^a, winding of PM^a, negative battery to ground, which responds and rotates the brushes step by step until a row of contacts, in which is included a set of contacts multiply connected with a line then idle, leading to the substation, is reached or until the last row of the group is reached, when the circuit for the magnet PM^a, owing to the disconnection of contact 1306 from ground, is interrupted, and owing to ground connection with the contact 1305 of the row, 75 circuit is established for the relay ST^a from grounded contact 1305, brush W⁴¹, contact 3 of PT^a, upper normal contact 2 and winding of SE^a, negative battery to ground which responds and, by the interruption of its normal and closure of its alternate contact 2, interrupts circuit for the flow of current through brush W⁴⁰ and establishes a holding circuit for the relay ST^a from ground, upper contact of PON^a, alternate 80 contact 3 of RR^a, alternate contact 2 and winding of ST^a, negative battery, to ground, which maintains the relay in its energized position so long as the alternate contact 3 of RR^a remains closed.
- 85 The closure of contact 1 of ST^a connects the magnet SM^a, over the upper heavily drawn conductors of the selected trunks, with the impulse transmitter. Thereafter, when the brush of the tens section reaches normal, the described energizing circuit for the relay RM^a of the units section of the impulse transmitter is established and the brush of the section restored to normal in the manner described, transmitting a single 90 impulse of current through the winding of SM^a, causing the brushes W²⁹ to W³⁹, inclusive, to be moved into connection with their first set of contacts 1301 to 1304, inclusive, respectively.
- 95 Thereafter, during the continued return to normal of the brush of the units section, the short circuit is, in the manner described, removed from around the winding of relay 1308, the relay energized, establishing a circuit for the flow of current through the winding of relay 1309, which responds, connecting ground with one terminal of the winding of relay LTR, whereby the busy or idle condition of the line is ascertained, and, if 100 idle, selected; or, if busy, following the de-energization of relay 1309 and the removal thereby of the short circuit from around the left-hand upper winding and lower winding of relay XT, the described vibratory circuit 105

is established for the magnet SM^6 , which rotates the brushes step by step into and out of connection with the passive contacts of the row until a set connected with an idle line leading to the desired substation is encountered; when the relay LTR is energized and such idle line connected with the connecting circuit; or, assuming the row selected to be the last row of the group and all lines connected to the passive contacts thereof leading to the desired substation to be busy, until the brushes engage the set of contacts leading to a line of some class other than the private branch exchange class, when the armature of the relay XT , in the manner described, is moved downwardly, interrupting the vibratory circuit for the relay SM^6 and establishing circuit for the relay BFR to connect the interrupter I^6 with the relay 746 ; to cause the flashing of the lamp 704 as described; or, if all lines of the row lead to the desired substation, until the brushes are moved one step beyond the last set of contacts of the row, when, owing to the disconnection of brush W^{38} from the last passive contact, the relay XT is de-energized, the vibratory circuit through magnet SM^6 interrupted, and, by the closure of the contact of SOR^6 , an energizing circuit is established for the flow of current through the lower winding of relay BFR , which responds and connects the interrupter I^6 , to cause the flashing of the lamp 704 to indicate to the operator that all paths leading to the desired substation are busy.

Referring again to the units section of the impulse transmitter, during its return to normal after the passage of its brush from connection with its sixth associated passive contact from normal, the contact 922 is interrupted and contact 973 closed; thereafter, during the movement of its brush between its fourth and second contacts inclusive, the contact 921 is closed.

The closure of contact 921 places a short circuit around the winding of relay 756 from contact 2 of RM^3 , contact 921 of the units section of the impulse transmitter, contact 1 of 812 , alternate contact 1 of RR^{14} , contact 1 of ST^{14} , brush $W^{20'}$, its engaged contact 802 , a terminal of the selected connecting circuit to one terminal of the winding of relay 756 , and, as the other terminal of the winding is, at the time, connected with ground through contact of key 707 and energized over a circuit including the winding of relay 810 and negative battery, the relay 756 is deprived of current and returned to normal, which establishes, by the closure of its normal contact 3, a circuit for the flow of current through the winding of relay 759 from ground, contact 2 of RR^3 , normal contact 4 of 757 , normal contact 3 of 756 , winding of 759 , negative battery, to ground, which responds, and by the closure of its contact 1

establishes the initial energizing circuit for the relay 747 , from ground, contact 1 of 759 , winding of the relay, negative battery, to ground.

The energization of relay 747 disconnects the traced ground connection with the test conductor of the connecting circuit and connects through the winding of coil 749 positive battery therewith, establishing the initial energizing circuit for the relay 760 from ground, contact 711 , left-hand winding of 760 , alternate contact 2 of 747 , winding of coil 749 , positive battery, to ground, and in multiple therewith from alternate contact 2 of 747 , contact 4 of 748 , now closed, normal contact 1 of 708 , normal contact 1 of 705 , test conductor multiply connected with 503 , brush W^{10} in engagement therewith, normal contact 2 of ST^7 , windings of polarized relay 506 to ground; also in multiple therewith over the last traced circuit, from normal contact 2 of ST^7 , contact 1 of 506 , left-hand normal contact of ST , brush W^2 in connection with the test contact 411 of the line of the calling substation, thence through the lamp LL or LL^2 , or lamps LL^3 , normal contact LR or LR^2 or LR^3 , as the case may be, to ground—contact 3 of the cut-off relay CO or CO^2 or CO^3 now interrupted.

It is to be understood that the line lamps LL , LL^2 are not illuminated when traversed by current through the winding of coil 749 in multiple with the relays 760 and 506 .

Restoration of impulse transmitters and connecting circuit finder switches. 00

The energization of relay 760 at this time removes the short circuit then existing through normal contact thereof and previously in multiple therewith, through normal contact 3 of 759 , from around the winding of coil 1009 , which decreases the flow of current over the circuit previously traced through the lower winding of differentially wound relay 1108 (Fig. 11) to an extent sufficient to cause the actuation of the relay, whereby its normal contacts are interrupted and its alternate contact closed, whereupon circuit is established for the relay 1109 , from ground, contact 1 of RR^4 , contact 3 of PON^4 , alternate contact of 1108 , winding of relay 1109 , negative battery, to ground, which responding, establishes a holding circuit therefore, traceable from ground, contact 1 of RR^4 , contact 3 of PON^4 , contact of GTR , contact 1 and winding of 1109 , negative battery to ground, whereby relay 1109 is maintained in its energized position during the closure of contact of GTR , or until the deenergization of relay RR^4 . 110 115 120 125

When the brush $W^{20'}$ of the units section of the impulse transmitter, during its return to normal, passes out of connection with its second passive contact from normal, the contact of 921 is interrupted, which removes the 130

previously traced short circuit from around the winding of relay 756, whereupon the relay 756 is energized over the previously traced circuit including the winding of relay 810, establishing circuit for the relay 757, from ground, contact 2 of RR³, normal contact 4 of 757, alternate contact 3 of 756, contact 2 of 759, winding of 757, negative battery to ground, which establishes a holding circuit from ground, contact 2 of RR³, alternate contact 4 and winding of 757, negative battery to ground, whereby the relay 757 is maintained in its energized position so long as the relay RR³ remains energized. The opening of normal contact 4 of 757 interrupts the holding circuit of relay 759, which returns to normal. The opening of the normal and closure of the alternate contact 1 of 757 disconnects interrupter I⁸ from connection with the lamp 703, preventing further flashing of such lamp, and establishes circuit for the steady flow of current through lamp 703, from ground, contact 2 of key 709, alternate contact 1 of 757, normal contact 3 of 758, lamp 703, negative battery to ground, which causes the lamp to burn steadily pending the response of the substation called, or if the substation called be busy, or if all paths leading to the multiple terminals thereof connected to the passive contacts of the final selectors be busy, the relay 758 is energized, a holding circuit therefor established over the traced path, through the alternate contact 3 and right-hand winding of relay 758, negative battery, to ground.

By the interruption of the normal and closure of the alternate contacts 2 and 3 of 757, the impulse transmitter is disconnected from the talking strands of the connecting circuit, and the section of the connecting circuit leading to the district selector and thence to the local incoming selector is connected with the section in which is included the relay 746, the right-hand windings of the repeating coil 753 and negative battery.

The deenergization of relay 759, responsive to the opening of normal contact 4 of 757 as described, places the previously described short circuit through normal contact 3 of 759 around the winding of coil 1009, which results in an increased flow of current through the lower winding of differentially wound relay 1108 to an extent sufficient to cause its deenergization, whereby its alternate contact is interrupted and its normal contacts closed, and by the opening of contact 1 of 759 the previously traced circuit through the relay 747 is interrupted—its holding circuit having been interrupted by the opening of normal contact 3 of 760, which returns to normal, disconnecting the coil 749 and positive battery from the test terminals of the connecting circuit and re-establishing, by the closure of normal con-

tact 2 of 747, the ground connection with the multiply connected test terminals 503 and 603 of the connecting circuit.

When the brush W^{20'} of the units section of the impulse transmitter reaches normal position, the described holding circuit through relay 812 is, by the opening of the contact 917 of each section of the impulse transmitter, interrupted, and the relay returned to normal, disconnecting the brushes W^{22'} and W^{23'} from connection with the impulse transmitter.

Following the return to normal of the brush W^{20'} of the units section of the impulse transmitter and the opening of contact 1 of relay 812, the energizing circuit of relay 810 is interrupted, the relay deenergized, and circuit for the flow of current established from ground, normal contact of PT¹⁴, contact 2 of PON¹⁴, contact 1 of 810, alternate contact 2 of RR¹⁴, winding of relay ST¹⁴, negative battery to ground, which energizes ST¹⁴, whereupon, by the opening of its contact 1 and normal contact 3, brushes W^{20'} and W^{21'} are disconnected. The closure of alternate contact 2 of ST¹⁴ establishes the previously described vibratory circuit through the winding of motor magnet SM¹⁴, which responds and moves the brushes W²⁰ to W²³ inclusive step by step into and out of connection with the remaining sets of passive contacts 802 to 805 inclusive of the row, until they are brought to the position one step beyond the last set of contacts of the row, when the brush W^{19'} is rotated to normal and the brushes W^{21'} to W^{23'} inclusive are rotated to the position above normal, whereupon the alternate contacts of PON¹⁴ are interrupted and their normal contacts closed. The interruption of contact 2 of PON¹⁴ interrupts the previously described circuits through the windings of relays ST¹⁴ and RR¹⁴, which return to normal, and, in respect to relay ST¹⁴, by the opening of its alternate contact 2, the vibratory circuit through the winding of motor magnet SM¹⁴ is interrupted, preventing its further actuation.

Simultaneous with the closure of normal contacts of PON¹⁴, the brushes W^{20'} to W^{23'} inclusive are rotated to normal position, whereupon the alternate contact of SON¹⁴ is interrupted and its normal contact closed.

Responsive to the deenergization of the relays 924 of each section of the impulse transmitter and the deenergization of relay RR¹⁴, the previously traced circuits through the windings of relay 814 are interrupted, whereupon the relay is restored to normal, and by the opening of its contact 2 the circuit through the left-hand winding of 811 is interrupted, whereby, upon the opening of contact 2 of PON¹⁴, relay 811 is deenergized, whence the connecting circuit finder

and all apparatus connected therewith are restored to normal position and placed in condition to be again actuated for the establishment of another connection.

5 *Operation of signaling the called subscriber.*

Reverting now to the differentially wound relay 1108 and the relay 1109, following the deenergization of the relay 1108, signaling current is connected to the line of the called substation, which may be traced from the signaling device not shown but multiply connected with the contact 1106 corresponding to the selected group; that is, the fifth 15 thousands group, thence through brush W^{20} in engagement therewith, winding of relay GTR, lower normal contact of relay 1108, alternate contact 3 of relay 1109, normal contact 1 of ST⁴, brush W^{25} , thence over the selected trunk through the hundreds selector, contact 1 of CR⁶, brush W^{26} , its engaged 20 passive contact 1301, a multiple terminal of the line of the called substation, thence over the conductors 101 or 201 or 301, as the case 25 may be, through the signaling mechanism of the substation, to ground, or returning over conductor 102 or 202 or 302, as the case may be, to the multiply connected passive contact terminal 1302, brush W^{27} in engagement therewith, contact 2 of CR⁶, thence over the 30 trunk line through the hundreds selector to multiply connected passive contact 1102, brush W^{28} in engagement therewith, contact 3 of ST⁴, alternate contact 2 of 1109, upper 35 normal contact of 1108, contact 3 of PON⁴, contact 1 of RR⁴ to ground.

As stated, the characteristics of the relays GTR are such that they are not sufficiently energized to interrupt their contact 40 when traversed by signaling current serially connected with the signaling apparatus of a substation, but the relays GTR are so constructed and adjusted as to be energized to open their contact upon the response of a 45 called substation. Therefore, when the called substation responds, the relay GTR is energized, its contact opened and the previously disclosed holding circuit therethrough of the relay 1109 interrupted. The 50 relay 1109 returns to normal, disconnecting the signaling current, and by closure of its normal contacts 2 and 3 establishes, as indicated by the heavily drawn lines, the conversational circuit between the calling substation and the called substation, such being inductively united by the repeating coil 753, and may be traced through the left-hand windings thereof over the heavily traced lines for the calling substation, and through 55 the right-hand windings of 753 over the heavily drawn lines for the called substation.

Upon the establishment of the conversational circuit between the calling and called

substations, following the closure as described of the contacts 2 and 3 of relay 1109, the relay 746, serially included in the lower talking strand of the section of the connecting circuit connected with the line of the called substation, is energized, interrupting 65 its normal contact and closing its alternate contact, establishing an energizing circuit through the left-hand winding of relay 758, which responds and by the opening of its normal contact 3 interrupts the previously 70 described circuit for the flow of current through the lamp 703, which is extinguished, visually indicating to the operator that the called substation has responded, and by the closure of the alternate contact 3 of 758, a 75 holding circuit from ground, contact 2 of 709, alternate contact 1 of 757, alternate contact 3 and winding of 758 is established, which holds the relay in its energized position until the time of disconnection of the 80 directly actuated selector switches, or until the actuation from normal of the ringing key 709.

75 *The function of interrupters I⁴ and I⁵.*

Referring now to the function of the interrupters I⁴, should all of the trunk lines terminating on the passive contacts of a directly selected group be, at the time of their attempted selection, busy or otherwise 95 unselectable, then as stated the contacts of SOR of the district selector, or local incoming selector or hundreds selector, as the case may be, will be closed, the interrupter I⁴ connected therethrough to the lower talking strand of the connecting circuit and thence, following the energization of relay 757, circuit from the interrupter I⁴ through the winding of relay 746 is established, and for each closure and interruption of the 100 brushes of I⁴ with a live one of their segments, the lamp 704 is caused to flash in a distinctive manner and thus visually indicate to the operator that all available paths to the line of the desired called substation 105 are unselectable, and that the connection cannot be established.

If the line of the called substation be of the individual-line class and busy, or if the line be of the multi-party class and at the 110 time busy, or if the called substation be of the private branch exchange class and all lines leading thereto be busy, following the energization of the relay BFR and the connection responsive thereto of the interrupter 115 I⁵ with the lower talking strand of the connecting circuit, the relay 746 is, following the disconnection of the impulse transmitter from the connecting circuit and the energization of relay 757, caused to vibrate, and 120 by openings and closures of its normal contact causes the lamp 704 to flash in a distinctive manner and visually indicate to the 125

operator that the path or paths leading to the called substation are busy and that the connection cannot be established.

5. *Operation of establishing a reverte connection.*

- Assuming the calling and called substation to be connected with the same line, then the described actuation of the relay 760 does not transpire, owing to the multiple connection with its left-hand winding of the coil 764, which acts to reduce the flow of current through the left-hand winding of the relay 760 to an extent sufficient to prevent its actuation. The multiple connection of coil 764 with the left-hand winding of relay 760 and in series with the winding of coil 749 to positive battery may be traced from ground, contact 711, contact 3 of RR³, winding of coil 764, normal contact 2 of 756, normal contact 2 of 757, thence over the upper heavily drawn line to the final selector, through alternate contact 3 of 1307, now energized, contact 3 of 1309, brush W⁸⁹, its engaged passive contact 1304, a multiple terminal of the line of the calling and called substations, contact 411, brush W² in engagement therewith, left-hand normal contact of relay ST of the line finder, contact 1 of 506, normal contact 2 of ST', brush W¹⁰ of the connecting circuit selector, engaged contact 503, a multiply connected test terminal of the connecting circuit, normal contact 1 of 705, normal contact 1 of 708, contact 4 of 748, alternate contact 2 of 747, winding of 749, positive battery to ground. Therefore, following the deenergization of 759, as described, the holding circuit of relay 747 from ground, contact 2 of RR³, normal contact 3 of 760, normal contact 3 of 709, contact 3 and winding of relay 747, negative battery, to ground is maintained, whereupon, following the deenergization of relay 759, the described circuit for the flow of current through the winding of relay 510 is interrupted; the relay returned to normal, which causes in a manner to be hereinafter described, the restoration to normal of the line finder and connecting circuit selector. Following the interruption of the holding circuit through the relay 510 and the disconnection of ground from the multiply connected test terminal 1308 of the final selector, the previously described circuit for the relay LTR is established, the relay actuated and the line selected.
- Following the energization of relay 747, by the energization of relay 757 and the failure of relay 760 to be actuated, circuit is established for the flow of current from ground, interrupter I³, alternate contact 4 of 747, normal contact 1 of 760, lamp 702, negative battery to ground, causing, for each closure of the brushes of interrupter

I³ with the live segments, the lamp 702 to 65 flash in a distinctive manner to visually indicate to the operator that the connection is "reverte."

The operator observing such flashing of the lamp 702, by operating the listening key 708 of the connecting circuit may request the calling subscriber to "hang up for a moment," which act on the part of the subscriber will be indicated by the illumination of lamp 704—the connection to the 75 line of the calling substation now existing through the final switch and the connection to the calling line through the line finder, and connecting circuit selector interrupted, the relay 746 is placed under the control 80 of the calling substation and jointly therewith under the control of the called substation). The operator observing the steady burning of the lamp 704, by operating the key 709 interrupts the traced holding circuit through the contact 3 of 709 for the relay 747, whereupon relay 747 returns to normal and interrupts the traced circuit through the interrupter I³ and lamp 702, preventing further flashing of such lamp, 90 interrupts the holding circuit through relay 758 which returns to normal, and by the opening of its contact 4 interrupts circuit through the lamp 704, whereby the same is extinguished. The opening of normal contact 4 of key 709 removes the described short circuit from around the winding of coil 1009, which, in the manner described, causes the energization of the differentially wound relay 1108, whereby the described energizing and holding circuits of the relay 1109 are established.

As the actuation of the key 709 may be momentary, upon the restoration thereof the short circuit around the winding of coil 1009 is again established, and the differentially wound relay 1108 deenergized, resulting, as described, in the connection of signaling current with the connected line, causing thereby the actuation of the signaling 110 mechanism of the called substation.

Upon the subsequent response by the called substation or by the calling subscriber, the relay 746 is again energized, followed by the energization of relay 758, whereby the 115 flow of current through the lamp 703 is interrupted, the lamp extinguished, and the lamps 702 and 704 placed in condition to have their circuits simultaneously closed when the calling and called subscribers 120 "hang up." During the existence of the "reverting" connection, the selection of the connecting circuit by a seeking connecting circuit selector or secondary connecting circuit selector is prevented, owing to the connection of ground through normal contact 2 of 747 or positive battery through winding of coil 749 via alternate contact 2 of 747

with the multiply connected test terminals 503 and 603 of the connecting circuit.

Operation of secondary connecting circuit selectors.

5 Considering now the operation of the secondary connecting circuit selectors, as previously set forth, if all of the connecting circuits, multiply connected to the passive contacts of a connecting circuit selector at the time of the selective operation of such selector, be busy, or if all of the operators, before whom such connecting circuit appears, be busy, then the brushes of the connecting circuit selector are rotated to the last row of sets of passive contacts to each of which is multiply connected a secondary connecting circuit selector, whereupon, by the disconnection of brush W^8 from the grounded contacts 501, the described holding circuit through relay PT' is interrupted, the relay deenergized and the initial energizing circuit of relay ST' established. The brushes W^9 to W^{12} inclusive are then, responsive to energizations of the motor magnet SM' , rotated step by step into and out of connection with their associated passive contacts 502 to 505 inclusive, multiple terminals of secondary connecting circuit selectors, until the 10 brushes engage a set connected with an idle secondary connecting circuit selector, when the holding circuit through the relay ST' , owing to the absence of ground connection with the contact 503 of such secondary connecting circuit selector, is interrupted and the relay deenergized, which interrupts circuit through SM' , leaving the brushes in connection with their associated multiply connected passive contacts, terminals of the 15 selected idle secondary connecting circuit selector.

Following the restoration of relay ST' , the initial energizing circuit of the relay PT^2 of the selected secondary connecting circuit selector is established from ground, normal contact 3 of 509, normal contact 3 of ST' , brush W^9 , its engaged passive contact 502, normal contact of PON^2 , winding of relay PT^2 , negative battery, to ground. The relay PT^2 responding, establishes a vibratory circuit from ground, alternate contact 1 of PT^2 , interrupter contact and winding of PM^2 , negative battery, to ground, resulting in the energization of PM^2 and the 20 movement of the brushes W^{13} to W^{17} one step from normal to the position opposite the first row or minor group of passive contacts 602 to 605 inclusive, when the brush W^{13} engages the corresponding group test 25 passive contact 601, the multiple test terminal of a minor group of connecting circuits appearing before an operator of a second team of fifteen operators. Should there be included in such minor group an idle connecting circuit and if the operator before

whom the connecting circuits of such minor group appears to be idle, then the relay PT^2 will be deenergized, and the circuit through PM^2 interrupted. If, however, and as assumed, all of the connecting circuits of the 30 group be busy or the operator before whom they appear be busy, the passive contact 601 will be connected with ground through a contact of relay 714, a relay 730, a relay 733 or a relay GBC' , with the result that 35 prior to the opening of the normal contact of PON^2 , by the engagement of the brush W^{13} with the contact 601, a holding circuit for the relay PT^2 is established from the grounded contact 601, brush W^{13} , alternate contact 2 and winding of PT^2 , negative battery, to ground, which maintains the vibratory circuit through the winding of magnet PM^2 , whereby the brushes W^{13} to W^{17} inclusive are rotated step by step from row to 40 row of passive contacts until the brush W^{12} engages a contact 601 corresponding to a minor group of connecting circuits, in which is included a connecting circuit then idle, and if the operator, before whom such idle 45 connecting circuit appears, is at the time idle, then the holding circuit through relay PT^2 , owing to the absence of ground connection with the group passive test contact 601, is interrupted, the relay deenergized, which, 50 by the opening of its alternate contact 1, interrupts the vibratory circuit through magnet PM^2 , preventing further rotation of the brushes in their primary selecting operation.

The closure of normal contacts 1 and 2 of PT^2 connects ground to the passive group test contact 602 traceable from normal contact 1 of PT^2 , alternate contact of PON^2 , now closed, contact 2 of RR^2 , normal contact 2 of PT^2 , brush W^{13} in engagement 55 with the said contact 601, which is multiply connected with corresponding contacts 601 of other secondary connecting circuit selectors, and also multiply connected to corresponding contacts 501 of a plurality of 60 connecting circuit selectors, which prevents, during the existence of such grounded connection with the contacts 601 and 501, the selection of the minor group of connecting circuits by either a connecting circuit selector or a secondary connecting circuit selector.

The closure of normal contact 1 of relay PT^2 also establishes a circuit for the flow of current from ground, normal contact 1 of PT^2 , alternate contact of PON^2 , contact of SON^2 , left-hand winding of relay ST^2 , negative battery, to ground, which energizes the relay ST^2 , and by the closure of its contact 3 establishes a circuit from ground, contact 3 of ST^2 , right-hand interrupter contact and winding of SM^2 , negative battery to ground, and in multiple therewith through left-hand interrupter contact of SM^2 , right-hand winding of ST^2 , negative 70

battery, to ground. The magnet SM^2 responding, moves the brushes W^{14} to W^{17} inclusive one step in their secondary selecting operation to connection with their corresponding contacts 602 to 605 inclusive, multiple terminals of the first connecting circuit of the selected minor group. Whereupon, if such connecting circuit be idle, the relay ST^2 will be deenergized and its contact 3 opened, whereby the circuit through SM^2 is interrupted and further rotation of the brushes W^{13} to W^{17} inclusive prevented.

If, however, as is assumed, the connecting circuit connected with the first set of contacts 602 to 605 inclusive, engaged by the brushes W^{13} to W^{17} inclusive, be busy, then ground is connected with the contact 603 and a maintaining circuit established for the relay ST^2 from grounded contact 603, brush W^{15} in engagement therewith, alternate contact 2 of ST^2 , normal contact 3 of RR^2 , left-hand winding of ST^2 , negative battery, to ground, which holds the relay ST^2 energized and the traced vibratory circuit through winding of SM^2 maintained, as, during the passage of the brushes from one set of contacts to the next succeeding set of contacts, the circuit of relay ST^2 is maintained over the circuit traced through its right-hand winding.

When the brushes W^{14} to W^{17} inclusive engage a set of passive contacts 602 to 605 inclusive, multiple terminals of an idle connecting circuit, the described maintaining circuit for the relay ST^2 through brush W^{15} is, owing to the absence of ground connection with the contact 603, interrupted, the relay deenergized, and by the opening of its contact 3, the described vibratory circuit for SM^2 is interrupted, preventing thereby further rotation of the brushes W^{14} to W^{17} in their selecting operation. The closure of normal contact 2 of relay ST^2 connects ground with the passive contact 603. Such connection at this time may be traced from normal contact 3 of RR^2 , normal contact 1 of 506, normal contact 2 of ST^2 , brush W^{16} , its engaged contact 503, normal contact 2 of ST^2 , brush W^{15} , its engaged contact 603, which acts to prevent the selection of the connecting circuit by any connecting circuit selector or secondary connecting circuit selector, to the passive contacts of which are connected its selective terminals.

Upon the selection of a connecting circuit by a secondary connecting circuit selector, circuits through the interrupters I' and I^2 (Fig. 5) are, as hereinbefore described, with the exception that their circuits extend through contact 1 of ST^2 and brushes W^{16} , W^{17} , established, whereby the class-of-service register is operated, following which the energizing circuit through the lower winding of relay 510 (the upper winding of relay 510 now short-circuited as a result of

the closure of contact 'POR') is established in the manner hereinbefore described, with the exception that when the connection extends through the secondary connecting circuit selector there is included in series 70 through brush W^{14} and contact 4 of relay ST^2 , the winding of relay 607, which is energized, and by the closure of its alternate contact establishes a circuit for the flow of current from ground, alternate contact 75 of PON^2 , alternate contact 1 of 607, relay RR^2 , negative battery, to ground, whereby the relay RR^2 is energized, establishing therefor a holding circuit from ground, normal contact 1 of PT^2 , alternate contact 80 of PON^2 , alternate contact 1 and winding of RR^2 , negative battery, to ground, which holds the relay in its energized position so long as the alternate contact of PON^2 remains closed. The interruption of contact 85 2 of RR^2 , following its energization, disconnects ground from the brush W^{15} , rendering, in so far as the connecting circuit selector is concerned, the connecting circuits of the minor group selectable by the 90 connecting circuit selectors and secondary connecting circuit selectors, to the passive contacts of which are multiply connected their selective terminals.

Restoration of line finder connecting circuit selector and secondary circuit selector.

During the selecting operation of a connecting circuit selector, responsive to the initiation of a call, should all of the connecting 100 circuits terminating on the passive contacts thereof be busy, or the operators before whom such connecting circuits appear be busy, the connecting circuit selector will, as hereinbefore described, select a secondary 105 connecting circuit selector; and if all of the connecting circuits multiply connected to the passive contacts of such selected secondary connecting circuit selector be busy, or if all of the operators before whom such 110 connecting circuits appear be busy, the brushes of the secondary connecting circuit selector will be rotated, in the manner described, one step beyond their last row or minor group of contacts, whereupon the relay PT^2 will be deenergized, interrupting the described circuit through PM^2 , preventing further rotation of the brushes in their primary selecting operation and closing the hereinbefore described initial energizing circuit for ST^2 , which responds and closes the described circuit through the magnet SM^2 , which is energized and moves the brushes W^{14} to W^{17} inclusive one step in their secondary selecting operation; whereupon, owing to the absence of connection of brush W^{15} with a contact 603, circuit through the relay ST^2 is interrupted, the relay restored to normal, interrupting there-by the vibratory circuit through the motor 120 125 130

magnet SM² and preventing further rotation of the brushes at this time.

Upon the brushes reaching their position one step beyond their last row of passive contacts, the contacts of POR² are closed, with the result that upon the selection by the line finder of its set of passive contacts, the multiple terminals of the line of the calling substation, or if, for any reason, the line finder fails to select a row or minor group of its passive contacts and close its contact POR, or if, following the selection by the line finder of a row of its passive contacts, the line finder, for any reason, 10 fails to select a set of its passive contacts, its brushes are rotated to the position one step beyond the last set of the selected row and the contact of SOR closed; whereupon circuit is established from ground, the live 15 segment and brush of interrupter I', contact 4 of RR', contact 1 of ST', right-hand winding of relay 509, normal contact 3 of 510, brush W¹², its contact 505 engaged, contact 2 of POR², winding of coil 608, negative 20 battery, to ground, which energizes the relay 509 and establishes circuit which may be traced from ground, normal contact 1 of PT², alternate contact of PON², normal contact 1 of RR², contact 1 of PÖR², winding 25 of relay 607, passive contact 502, brush W³ in engagement therewith, normal contact 3 of ST', alternate contact 3 of 509, lower winding of coil 510, contact of POR', normal contact 2 of 506, contact 3 of ST, 30 brush W³ and its engaged passive contact 412, a multiple terminal of the line of the calling substation to winding of the cut-off relay CO, or CO², or CO³, as the case may be, negative battery, or positive battery, to 35 ground, which energizes the relays 510 and 607, following which, by the closure of contact 1 of 510, the energizing circuit for the relay 508, as hereinbefore described, is established, which responds and establishes 40 the initial energizing circuits, as described, for the relays RR and RR'. 45

The closure of the alternate contact of 607 establishes the energizing and holding circuits for the relay RR². Following the 50 energization of relay RR², the described circuit for the flow of current through the winding of relay 607 and the lower winding of relay 510 is interrupted, the relays de- 55 energized, causing, in the manner to be herein- 60 after described, the restoration to normal of the line finder, the connecting circuit selector and the secondary connecting circuit selector, whereupon, had the line of the calling substation been selected by the line finder and the apparatus of the sub- 65 station still in its call initiating condition, a second line finder and its link connecting circuit selector will be started, the line finder seeking to select the line and the connecting

circuit selector seeking to select a connecting 65 circuit in the manner described.

Operation of various pieces of apparatus associated with the connecting circuit.

(A) Reringing key.

70

After the establishment of connection with a called substation, should it be desirable to resignal such called substation, the operator will momentarily actuate from normal the key 709 and, by the opening of normal contact 4 thereof, remove, in the manner described, the existing short circuit from around the winding of coil 1009, whereby the winding of the coil will be brought into serial circuit connection with the lower 80 winding of relay 1108, reducing the flow of current therethrough to an extent sufficient to cause actuation of the relay 1108, to interrupt its normal contacts and close its alternate contact. The closure of the alternate contact establishes the previously traced energizing circuit for the relay 1109, which responds and, by the closure of its contact 1, establishes its holding circuit, with the result that upon the release of the key 709 85 and the reclosure of its normal contact 4, the short circuit around the winding of coil 1009 is again established, causing the flow of current through the lower winding of relay 1108 to be increased to an extent such 90 as to cause its deenergization, thereby interrupting its alternate contact and closing its normal contacts, connecting, in the manner described, signaling current with the line of the called substation to cause the actuation 95 of the signal or signals thereof. Thereafter, upon the response of the subscriber at the called substation, the relay GTR is actuated, its contact opened, interrupting the holding 100 circuit through the relay 1109, which is de- 105 energized, its alternate contacts interrupted, which disconnects signaling current from the line of the called substation, and by the closure of its normal contacts 2 and 3 re- 110 establishes the conversational circuit.

(B) Listening key.

In order that the operators may, while establishing and during the existence of a connection, "listen in", a key 708 is provided 115 for each connecting circuit, each of which, when actuated from normal by the closure of its contact 2, establishes a circuit from ground, through lower winding of differentially wound relay 732, contact 2 of 708, 120 winding of relay 733, negative battery, to ground, which energizes the relay 733, and by the closure of the alternate contacts of 733 connects ground with the test conductors multiply connected to the passive contacts 501 and 601 of each connecting circuit selector and secondary connecting circuit selector, to the passive contacts of which 125

are connected the selective terminals of the connecting circuits of the secondary group, rendering thereby each minor group of the secondary group unselectable by any such 5 connecting circuit selector or secondary connecting circuit selector. The closure of contact 3 of an actuated key 708 establishes circuit from ground, contact 3 of 708, brush W¹⁸, its engaged contact 710, the lamp 734 10 connected therewith, negative battery, to ground, which causes the illumination of such lamp to visually indicate to the operator the class of the line of the calling substation connected with the connecting circuit of the actuated key 708.

The closure of contact 4 of an actuated key 708 establishes the previously described circuit through the upper windings of relays 732 and 755, whereby the relay 755 is energized and the operator's telephone connected with the talking strands of the connecting circuit, enabling the operator to converse with the calling subscriber and with the called subscriber, if at the time of actuation 25 of the key 708 a called substation be in connection with the connecting circuit.

Should the key 708 of a connecting circuit be actuated during the automatic connection of the operator's telephone with some 30 other connecting circuit of the secondary group, then such automatic connection of the operator's telephone would, during the actuation of the key 708, responsive to the opening of the right-hand normal contact of relay 733, be interrupted. Thereafter, upon the restoration of the key 708 and the de-energization of relay 733 by the closure of the right-hand normal contact of 733, such automatic connection of the operator's telephone will, unless, as described, the recording keys of the position had in the meantime been actuated, be reestablished.

(C) *Line flash key.*

45 After the operation of the key 708 of a connecting circuit by the actuation from normal of the common key 720, circuit is established to cause illumination of the line lamp LL, or LL², or the lamps LL³, depending upon the class of the line of the calling substation connected with the connecting circuit of the actuated key 708, which may be traced from ground, normal contact of relay LR, or LR², or LR³, through the associated line signal lamp LL, or LL², or LL³, passive contact 411, brush W² in engagement therewith, normal contact 1 of ST of the line finder, contact 1 of 506, normal contact 2 of ST', brush W¹⁰, its engaged passive contact 503 of the connecting circuit selector, normal contact 2 of ST², brush W¹⁵, engaged passive contact 603,—if the connection extends through a secondary connecting circuit,—normal contact 1 of key 705, alternate contact 1 of key 708, thence over the

common conductor, alternate contact of key 720, positive battery, to ground.

(D) *Coin-return key.*

If, after the actuation of a listening key 708 of a connecting circuit in connection with a substation of the coin box class, it be necessary to return to the subscriber a deposited coin, the operator will actuate common key 722 and establish thereby a circuit which may be traced from ground positive battery, winding of coil 767, alternate contact 1 of 722, contact 3 of 732, contact 1 of 755, winding of relay 750, normal contact 2 of 758 to ground, or alternate contact 2 and left-hand winding of 758, negative battery, to ground. Relay 750 responding, circuit is established from ground, through generator 771, from the negative pole thereof, upper winding of 736, contact 2 of 722, normal contact of 723, normal contact 1 of 724, normal contact 2 of 729, contact 2 of 732, normal contact 1 of 706, alternate contact 1 of 750, contact 2 of 705, thence over the upper heavily drawn conductors to the substation, through the coin mechanism thereof, to ground; whereby, upon the actuation of such coin box mechanism, a deposited coin is restored to the subscriber and circuits established to cause flow of current through the upper winding of relay 736 of sufficient strength to cause the actuation of the relay and the closure thereby of its contact, which establishes circuit for the flow of current through the lamp 737, causing its illumination to indicate to the operator that the deposited coin has been returned. The operator, upon observing the lighted lamp 737, will release key 722, which restores to normal, and by the opening of its alternate contacts interrupt the traced circuit for the relay 736, which is deenergized, opening its contact, whereby the circuit through lamp 737 is interrupted and the lamp extinguished.

The restoration of key 722 also, by the opening of its contact 1, interrupts the energizing circuit of the relay 750, which deenergizes and establishes the connection of the line of the calling substation with the repeating coil 753 of the connecting circuit and with the operator's telephone, so long as the key 708 remains in its off-normal actuated position.

(E) *Coin-collect key.*

If, during the existence of the connection of a line of the coin box class with the connecting circuit, it be desirable to collect a deposited coin without interrupting the connection of the line with the connecting circuit, the operator will, during the actuation from normal of the key 708 of the connecting circuit, actuate key 723, which establishes a circuit from ground, positive battery, winding of coil 767, contact 1 of 723,

contact 3 of 732, contact 1 of 755, winding of 750, normal contact 2 of 758, to ground, or alternate contact 2 and left-hand winding of 758, negative battery to ground. The relay 750 is thereby energized and a circuit established from ground, through generator 770, from the positive pole thereof, through the lower winding of 736, alternate contact 2 of 723, normal contact 1 of 724, 5 normal contact 2 of 729, contact 2 of 732, normal contact 1 of 706, alternate contact 1 of 750, thence over the upper heavily drawn conductor to the substation, through the coin box mechanism thereof to ground, causing 10 thereby the collection of a deposited coin and the actuation of relay 736 which, by the closure of its contact, establishes circuit for the flow of current through lamp 737, which is illuminated and visually indicates to the operator the collection of the deposited coin; whereupon the operator will release the key 723, which restores to normal, and interrupt the flow of current from the generator 770 over the line, whereby the 15 relay 736 is deenergized, its contact opened, and the lamp 737 extinguished.

The opening of contact 1 of 723, responsive to its restoration to normal, interrupts the traced circuit for relay 750, which is deenergized, and reestablishes the connection of the calling substation with the repeating coil 753 of the connecting circuit and with the called substation, if connection thereto exists.

35 (F) *Disconnect and collect key.*

After the establishment of the connection and the completion of the conversation thereover, when the subscriber at the calling 40 substation "hangs up", circuit for the flow of current through the calling supervisory relay 751 is interrupted, the relay deenergized and circuit established from ground, contact of 707, normal contact 4 of 706, contact 2 of 732, contact 713, normal contact of 751, alternate contact 1 of 760, lamp 702, negative battery, to ground, which causes the illumination of the lamp 702.

When the subscriber at the called substation "hangs up", the previously described circuit through the relay 746, in which is included the called substation, is interrupted, the relay deenergized and circuit established from ground, normal contact of 746, contact 4 of 758, lamp 704, negative battery to ground, whereby the lamp 704 is illuminated.

The simultaneous illumination of lamps 702 and 704 visually indicates to the operator that conversation over the connection 60 has been completed and that disconnection should take place.

If the calling substation be equipped with a coin box or a substation message register, or if the line of the calling substation be

equipped with a central office message register MR (Fig. 1), MR² (Fig. 2), the operator will cause disconnection by actuating the key 706 of the connecting circuit from normal, which interrupts its normal contact 4, and by so doing interrupts the holding 70 circuit through relay 752, which returns to normal and interrupts the traced circuit through the lamp 702, which is extinguished, and establishes circuit from ground, contact of 707, alternate contact of 706, 75 winding of relay 750, alternate contact 2 and left-hand winding of relay 758, negative battery to ground, resulting in the energization of relay 750, which, by the opening of its normal contacts 1 and 2, 80 interrupts the connection of relays 751 and left-hand windings of the repeating coil 753 with the line, and by the closure of its alternate contact 1 establishes a circuit, assuming the calling substation to be equipped with a 85 coin box or substation message register, from ground through direct current generator 770, thence from the positive pole thereof, through the lower winding of relay 736, alternate contact 1 of 706, alternate contact 1 of 750, contact 2 of 705, thence over the upper heavily drawn conductor through the secondary connecting circuit selector (if such be included in the connection), the connecting circuit selector, 95 line finder, thence over the line through the coin box electromagnetic mechanism or the substation register to ground, which actuates such coin box apparatus to collect a deposited coin or actuates the substation message register to record the connection; whereupon the relay 736 is energized, its contact closed and circuit established therethrough for the lamp 737, which is illuminated to visually indicate to the operator that a deposited coin has been collected or that the 105 substation message register has been actuated.

Responsive to the actuation of key 706, assuming the line of the calling substation 110 to be equipped with a central office message register MR or MR², circuit is established from ground, winding and normal contact 1 of relay 741, alternate contact 3 of 706, alternate contact 3 of 750, and thence 115 through contact 602, brush W¹⁷ in engagement therewith, normal contact 4 of ST², winding of relay 607 of the secondary connecting circuit selector (if such be included in the connection), contact 502, brush W⁹ 120 in engagement therewith, normal contact 3 of ST', alternate contact 3 of 509, lower winding of relay 510, contact of POR', normal contact 2 of 506, contact 3 of ST, brush W³, its engaged contact 412, the multiple 125 terminal of the line of the calling substation, thence through the windings of message register MR, negative battery, to

- ground, or through the winding of message register MR^2 , positive battery, to ground, as the case may be, and in multiple therewith the relays CO or CO^2 .
- 5 The relay 741 responding thereto, by the opening of its normal contact 1 and the closure of its alternate contact 1, interrupts its initial energizing circuit and establishes a substitute circuit therefor, which may be 10 traced from ground, winding and alternate contact 1 of relay 741, contact of relay 742, winding of coil 766, negative battery, to ground. By the closure of contacts 2 and 3 of relay 741, circuit over the previously 15 traced paths is established through the right-hand windings of relays 743 and 744, whereupon, if the line of the calling substation be of the individual line class, the relay 744 will be energized, which, by the 20 opening of its normal contact, will interrupt the circuit through relay 743, and by the closure of its alternate contact 2 will short-circuit its left-hand winding, causing the flow of current to be increased over the 25 circuit through the winding of the message register MR to an extent sufficient to cause its actuation to interrupt its normal contact, close its alternate contact and record the connection. By the closure of the alter- 30 nate contact of MR , its lower winding is short-circuited, which still further increases the flow of current over the traced circuit, through the upper winding of magnet 765, to an extent sufficient to cause its actuation 35 to record the connection and to close its contact, and thereby establish circuit for the flow of current through the lamp 745, which is illuminated to visually indicate to the operator that the message register MR 40 has been actuated. Should the line of the calling substation be of the private branch exchange class, then the circuit would extend from negative battery through the lower winding of 765 and the winding of 45 relay 743, thence through the message register MR^2 , whereupon the operations respecting the register MR^2 , the relay 743 and magnet 765, would be as explained in connection with the message register MR .
- 50 The closure of contact 1 of relay 743 or contact 1 of relay 744 establishes in multiple with the coil 766 an energizing circuit for the slow release relay 742, and upon its actuation, a substitute holding circuit for the 55 relay 741. Thereafter, upon the restoration of the key 706 and the deenergization thereby of the relay 750, the traced circuit to the central office line message register is interrupted, the relay 743 or 744, as the case may 60 be, and the magnet 765 deenergized, which, in respect to the magnet 765, by the opening of its contact, extinguishes the lamp 745, and in respect to the relay 743 or 744, by the opening of its contact 1, the traced circuit 65 through the relays 741 and 742 is inter-
- rupted. The relay 741 is immediately restored, which, by the opening of its contact 2, interrupts the connection of the relays 743 and 744, and as the relay 742 is slow to release, the relay 741 is, by the continued interruption of the contact of 742, prevented from being again energized. 70
- Should the line of the calling substation be of the private branch exchange class, then upon the interruption of the normal 75 contact and the closure of the alternate contact 1 of the relay 741, the direction of flow of current through the winding of 741 will be reversed. The characteristic of the relay 741 is such, however, that its armature 80 will not be restored responsive to such reversal.
- Responsive to the actuation of the key 706 from normal as described, by the opening of normal contact 4 thereof the described holding circuit through the relay 752 is interrupted, which is deenergized and establishes a vibratory circuit from ground, normal contact 3 of 752, contact 3 of 748, interrupter contact and winding of MM' , negative battery, to ground. The magnet MM' 85 responding, rotates brushes W^4 step by step out of connection with the contacts 710, whereupon the contacts 711, 712, 713 are interrupted. The opening of contact 712 in- 90 terrupts the holding circuit through relay 748, which is deenergized and interrupts, by the opening of its contact 4, the previously existing connection of ground with the passive contacts 503 and 603, whereby, upon 95 the establishment of the releasing circuits of the connecting circuit selectors and line finder, the connecting circuit is rendered selectable.
- The operator, upon observing the lighted 100 condition of the lamps 737 or 745, will release key 706, which restores to normal, interrupting the traced energizing circuit through the relay 750, which returns to normal, and by the opening of its alternate contact 3 interrupts the holding circuit then existing through alternate contact 3 of 760 through the relays 741, 743 or 744 and magnet 745 for the relay 607, (assuming a secondary connecting circuit selector to be in- 105 cluded in the connection), relay 510 and the cut-off relay CO , or CO^2 of the line of the calling substation, when, owing to the interruption of contact 4 of relay 752 the relay 607—(if the connection extend through a 110 secondary connecting circuit selector)—relay 510 and relay CO or CO^2 , as the case may be, are deenergized. The contact 3 of 752 being interrupted and the relay 748 deenergized, responsive to the interruption of 115 the alternate contact 4 of relay 750, the holding circuit through relay RR^4 is interrupted, whereupon the relay RR^4 is deenergized, which by the opening of its normal contact 2 120 interrupts the holding circuit of relay 757, 125 130

which is deenergized and interrupts (if energized) the holding circuit of relay 760.

The deenergization of relay 757, by the opening of its alternate contact 1, interrupts the then existing circuit for the flow of current through the right-hand winding of relay 758 which, upon the restoration of key 706 and thereby the interruption of flow of current through its left-hand winding, is deenergized, interrupting the flow of current through lamp 704, which is extinguished.

The deenergization of relay 607 establishes circuit for the flow of current from ground, alternate contact 2 of PON², normal contact of 607, alternate contact 3 of RR², left-hand winding of relay ST², negative battery to ground, which energizes relay ST², establishing the previously traced vibratory circuit through the winding of SM², which rotates the brushes W¹⁴ to W¹⁷ inclusive step by step to the position one step beyond the last set of their associated passive contacts, when the brush W¹³ is rotated to normal and the brushes W¹⁴ to W¹⁷ inclusive to the position above normal. Thereupon, the alternate contact of PON² is opened, interrupting circuit of the relay ST² which is deenergized, and by the opening 30 of its contact 3, circuit of magnet SM² is interrupted, preventing thereby further actuation of the magnet. Simultaneously therewith, by the opening of alternate contact of PON², the holding circuit for the relay RR² is interrupted and the relay deenergized. Also, when the brush W¹⁸ reaches normal position, the brushes W¹⁴ to W¹⁷ inclusive are rotated to their normal position in the manner described in the 40 identified Kaisling patent, whereupon the contact of SON² is closed, and the switch placed in position to be utilized in establishing another connection.

The deenergization of relay 510, by the opening of its contact 1, interrupts circuit for the flow of current through the winding of relay 508, which deenergizes, interrupting the holding circuit then existing through alternate contact 2 of 508 for the relay 509, which deenergizes.

The deenergization of 508 establishes an energizing circuit for the relay ST' from ground, left-hand normal contact of PT', alternate contact of PON', normal contact 55 3 of 508, alternate contact 3 of RR', left-hand winding of ST', which responds and establishes the vibratory circuit, as previously described, through the winding of magnet SM', which responds and rotates the brushes W⁹ to W¹² inclusive step by step to the position two steps beyond the last set of passive contacts 502 to 505 inclusive of the row. Thereupon the brush W⁸ is restored to normal, and the brushes W⁹ to W¹² inclusive rotated to the position above nor-

mal, when the alternate contact of PON' is opened, and simultaneously therewith the brushes W⁹ to W¹² inclusive are restored to normal position.

The opening of alternate contact of PON' 70 interrupts the previously traced holding circuit for relay RR' and the circuit for the flow of current through the left-hand winding of ST'. The relays RR' and ST' are deenergized, whereupon, by the opening of 75 the alternate contact 3 of ST', the vibratory circuit through SM' is interrupted, preventing its further actuation. When the brushes W⁹ to W¹² inclusive reach their normal position, the alternate contact of SON' is 80 opened, its normal contact closed, and the switch placed in condition to be used in the establishment of some other connection.

The closure of contact 1 of 508 establishes circuit from ground, normal contact of PT, 85 alternate contact of PON, normal contact 1 of 508, alternate contact 1 of RR, right-hand winding of ST, negative battery, to ground, which causes the energization of relay ST and thereby establishes the previously described vibratory circuit through the winding of magnet SM, which responds and rotates the brushes W² to W⁵ inclusive step by step until they reach the position two steps above the last set of contacts of 95 the row, when the brush W' is rotated to normal position, and the brushes W² to W⁵ inclusive to the position above normal, when the alternate contact of PON is opened, interrupting the traced holding circuit of 100 relay RR, and the circuit, through the normal contact 1 of 508, for the relay ST, causing thereby the deenergization of relays RR and ST.

The opening of contact 2 of ST interrupts 105 the vibratory circuit through the winding of magnet SM, preventing its further actuation. Simultaneously with the interruption of the alternate contact of PON, the brushes W² to W⁵ inclusive are rotated to normal 110 position, whereupon the contact of SON is closed and the switch placed in condition to be used in establishing another connection.

The opening of alternate contact 3 of RR and the opening of alternate contact 1 of 115 RR' disconnects ground from the corresponding passive contact 418 of the allotter, rendering the line finder and connecting circuit selector allottable, whereby, responsive to the closure of the alternate contact of an 120 associated relay GBC, the line finder and connecting circuit selector may be started, the line finder to select the line of the calling substation, and the connecting circuit selector to select an idle connecting circuit appearing before an operator then idle, or to select a secondary connecting circuit selector as previously described.

Referring now to the restoration of the 130 district selector (Fig. 10), responsive to the

closure of normal contact 1 of relay RR³, circuit is established for the relay ST³ from ground, alternate contact of PON³, normal contact 1 of RR³, winding of ST³, negative battery to ground. The relay responding, by the interruption of its normal contact 4, disconnects ground from the brush W²¹, whereby the circuit for the relay RR⁴ is interrupted and the relay deenergized, establishing the restoring circuits for the local incoming selector.

The closure of contact 2 of ST³ establishes the vibratory circuit for the motor magnet SM³, which responds and rotates the brushes W¹⁹ to W²¹ inclusive step by step, until they have reached the position two steps beyond the last set of passive contacts of the row. Thereupon the brushes W²² to W²⁴ are rotated to normal position and the brushes W¹⁹ to W²¹ to the position above normal, whereupon, by the opening of alternate contact of PON³, the circuit for relay ST³ is interrupted, the relay deenergized, its contact 2 opened, interrupting the vibratory circuit through the winding of motor magnet SM³, preventing its further actuation.

Simultaneous with the opening of the alternate contact of PON³, the brushes W¹⁹ to W²¹ inclusive are rotated to their normal position, the alternate contacts of SON³ interrupted and the normal contacts thereof closed, placing the selector in condition to be used in establishing another connection.

Responsive to the deenergization of relay RR⁴, by the opening of its contact 1, the flow of current through the upper winding of relay 1108 and through the winding of relay 1109 is interrupted, which deenergizes. The deenergization of RR⁴ establishes circuit for the flow of current from ground, alternate contact 1 of PON⁴, normal contact 4 of RR⁴, winding of ST⁴, negative battery, to ground, which causes the energization of relay ST⁴, whereupon, by the opening of its normal contact 4, ground is disconnected from the test brush W²⁷, interrupting thereby the holding circuit of relay RR⁵ of the hundreds selector, which deenergizes and establishes the restoring circuits of the hundreds selector.

The closure of alternate contact 2 of relay ST⁴ establishes the vibratory circuit for the motormagnet SM⁴, which responding, rotates the brushes W²⁵ to W²⁷ inclusive step by step to the position two steps above the last set of passive contacts of the row. Thereupon the brushes W²⁸ to W³⁰, inclusive, are rotated to normal, and the brushes W²⁵ to W²⁷ inclusive are rotated to the position above normal, when the alternate contacts of PON⁴ are interrupted and the normal contact thereof closed, interrupting thereby the circuit of relay ST⁴, which deenergizes and, by the opening of its contact

2, interrupts the vibratory circuit through the winding of motor magnet SM⁴, preventing its further actuation. Simultaneous with the closure of normal contact of PON⁴, the brushes W²⁵ to W²⁷ inclusive are rotated to normal position, whereupon the alternate contact of SON⁴ is opened and the normal contacts thereof closed, placing the local incoming selector in condition to be utilized in establishing another connection. 75

Following the deenergization of relay RR⁵ as described, circuit is established from ground, alternate contact 2 of PON⁵, normal contact 3 of RR⁵, winding of ST⁵, negative battery, to ground, which energizes the relay ST⁵, disconnecting, by the opening of its normal contact 4, ground from the brush W³³, which interrupts the existing holding circuit for the relay RR⁶ of the final selector, which deenergizes and establishes circuits 85 which cause the restoration of the final selector.

The closure of contact 2 of ST⁵ establishes a vibratory circuit for the motor magnet SM⁵, which responds and rotates the brushes W³¹ to W³³ inclusive step by step to the position two steps above the last set of contacts of the row, whereupon the brushes W³⁴, W³⁵ are restored to normal and the brushes W³¹ to W³³, inclusive, are rotated to the position above normal. Thereupon, the alternate contacts of PON⁵ are opened and its normal contact closed, resulting, by the opening of contact 2 thereof, in the interruption of circuit for the flow of current 100 through the winding of relay ST⁵ which deenergizes, and by the opening of its contact 2 interrupts the vibratory circuit through the winding of motor magnet SM⁵, preventing its further actuation. 105

Simultaneous with the closure of the normal contact of PON⁵, the brushes W³¹ to W³³, inclusive, are rotated to normal position, the alternate contact of SON⁵ opened and its normal contacts closed, placing the 110 switch in condition to be utilized in establishing another connection.

Responsive to the deenergization of relay RR⁶, the then existing circuit through the relay ST⁶, by the opening of contact 3 of RR⁶, is interrupted, the relay ST⁶ deenergized, establishing circuit from ground, upper alternate contact of PON⁶, normal contact 3 of RR⁶, upper winding of BFR, negative battery, to ground, which energizes the 120 relay BFR, interrupting, by the opening of its normal contact 1, the then existing holding circuit through the winding of relay 1307, which deenergizes, and, by the opening of its contact 1, disconnects the relay 125 LTR from the brush W³⁸, interrupting thereby the circuit for the flow of current through the winding of the relay LTR and the winding of relay CO, or CO² or CO³, as the case may be, of the line of the called sub- 130

station, which deenergizes, placing the line of the called substation in condition whereby calls may be initiated thereover, or the substation or substations thereof may be, as 5 called substations, selected.

Responsive to the energization of relays BFR, a holding circuit therefor is established from ground, contact of SON^a, alternate contact 1 and lower winding of relay 10 BFR negative battery to ground, which holds the relay in its energized position as long as the contact of SON^a remains closed.

By the closure of alternate contact 2 of BFR, ground is connected through the normal contact 2 of RR^a to the contact 1203 which guards the trunk from seizure during the interval elapsing between the movement of the brush W³³ from off contact 1203 until the connector switch of Fig. 13 is fully 20 restored.

In multiple with the traced circuit through the upper winding of relay BFR, a circuit is established for the flow of current from ground, upper alternate contact 25 of PON^a, normal contact 3 of RR^a, right-hand winding of upper coil of XT, negative battery to ground, which energizes relay XT in a manner to cause the actuation of its armature in a direction such as to close 30 the alternate contact 1 thereof, and establish a vibratory circuit for the magnet SM^a from ground, normal contact 1 of LTR, interrupter contact of SM^a, alternate contact 1 of XT, winding of SM^a, negative battery, to ground, which responds and 35 rotates the brushes W³⁶ to W³⁹ inclusive step by step to the position two steps beyond the last set of contacts of the row. Thereupon the brushes W⁴⁰, W⁴¹ are rotated to 40 normal position, the brushes W³⁹ to W³⁶, inclusive rotated to the position above normal, the alternate contacts of PON^a opened and its normal contact closed, resulting in the interruption of the circuit through the 45 upper winding of BFR and the right-hand winding of the upper coil of XT, deenergizing the relay XT and, by the opening of its alternate contact 1, the vibratory circuit through the winding of motor magnet SM^a 50 is interrupted, preventing its further actuation.

Simultaneously with the closure of the normal contact of PON^a, brushes W³⁶ to W³⁹, inclusive, are rotated to normal position when the contact of SON^a is opened, which interrupts the holding circuit through the lower winding of BFR, causing thereby its deenergization.

The deenergization of the relay LTR, responsive to the opening of contact 1 of 1307, by the opening of its contact 2 interrupts the then existing circuit for the flow of current through the winding of relay CR^a, which deenergizes and, by the opening of 65 its contacts 1 and 2, disconnects the brushes

W³⁶, W³⁷. Thus during the restoring operation of the switch, the brushes W³⁶, W³⁷ are, when passing into and out of connection with the associated contacts 1301, 1302 respectively, disconnected. 70

(G) *Disconnect without register or collect key.*

Should the line of the calling substation be of the "flat-rate" class, or, as sometimes expressed, of the "unlimited" class, or in the event of failure of response by the called subscriber, which is indicated by the illumination of lamp 703, or if the line of the called substation, at the time of attempted connection, be busy, which is indicated by a distinctive flashing of the lamp 704, or, if all the available paths to the called terminals of the line or lines of the called substation be, at the time of attempted connection, unselectable, which is indicated by a distinctive flashing of the lamp 704, the operator, after observing the lighted condition of lamps 702 and 703 or 704, actuates the key 707 from normal, and 80 interrupts thereby the existing energizing circuit for the flow of current through the winding of relay 752 and the holding circuit in multiple therewith of the relay RR^a, which are deenergized, and in respect to 85 relay 752, by the opening of its contact 4, the holding circuit through relay 607, (if the connection extended through a secondary connecting circuit selector), relay 510 and relay CO, or CO², or CO³, depending upon the class of the line of the calling substation, is interrupted, whereupon relays 607, 510 and CO, or CO² or CO³ are deenergized, following which the secondary connecting circuit selector (if employed), 90 the connecting circuit selector and line finder are restored to normal, as previously described. 95

Responsive to the deenergization of relay RR^a, as a result of the actuation from normal of key 707, the district selector, local incoming selector, hundreds selector and final selector, or such of them as were operated from normal, are restored in substantially the same manner as previously 105 described. 110

(H) *Disconnect key No. 721.*

If, during the existence of connection of a calling substation of the coin-box class, substation message register class, or central office message register class, it be desirable or necessary to disconnect the line of the called substation without also disconnecting the line of the calling substation, and 120 without actuating the coin box apparatus or substation message register, or central message register, as the case may be, the operator, after operating key 708, will actuate from normal the key 721, which establish- 125 130

- lishes circuit for the flow of current from ground, positive battery coil 767, alternate contact of 721, contact 3 of 732, contact 1 of 755, winding of 750, normal contact 2 of 758 to ground, or alternate contact 2 and left-hand winding of 758, negative battery to ground, which energizes the relay 750, whereupon, by the opening of normal contact of 721 and the normal contact 4 of 750,
- 10 the holding circuit of relay RR³ is interrupted, the relay deenergized, establishing the hereinbefore traced restoring circuits for the district selector, causing its restoration, and effects, in the manner described,
- 15 the restoration of the local incoming selector, the hundreds selector, and final selector, rendering such switches available for use in establishing other connections, and the line of the called substation selectable either as
- 20 a calling or called line.

(I) *Disconnect key No. 724.*

- If, during the existence of the connection of a calling substation of the coin-box class, 25 substation message register class or central message register class, and after the called party has "hung up", it be desirable to collect a deposited coin, actuate the substation message register or actuate the central office message register, as the case may be, hold the line of the calling substation and disconnect the line of the called substation, the operator, after actuating from normal the key 708, will actuate from normal the 30 key 724, which establishes circuit from ground, normal contact of 721, alternate contact 3 of 724, thence over the previously traced path through the winding of 750, alternate contact 2 and left-hand winding 35 of 758 (now energized), negative battery, to ground, which energizes relay 750 and establishes circuit if the line be of a coin box class, or substation message register class, from ground, generator 770, from the positive pole thereof, alternate contact 1 of 724, normal contact 2 of 729, contact 2 of 732, normal contact 1 of 706, alternate contact 1 of 750, and thence over the upper 40 heavily drawn conductor to the substation; 45 through the coin box mechanism or through the substation message register thereof, which actuates such coin box mechanism to collect a deposited coin or the substation message register to record the connection; 50 or if the line be of the central office message register class, responsive to the energization of relay 750 and the closure of its alternate contact 3, circuit is established from ground, winding of 741, alternate contact 2 55 of 724, alternate contact 1 of 732, and thence over the previously traced path through the windings of message register MR and through the winding of the relay CO, negative battery, to ground, or through the 60 windings of MR² and CO², positive battery,

to ground, resulting in the actuation of such message register and, as described, in the actuation of the position message register, including the relay 741 and magnet 765. By the opening of normal contact 3 of 724 70 and the normal contact 4 of 750, the holding circuit through the relay RR³ is interrupted, the relay deenergized, causing, in the manner described, the restoration of the district selector, local incoming selector, hundreds selector and final selector to their normal condition. 75

(J) *Holding key.*

In order to release the line of a calling 80 substation, whereby such line may be employed as a calling or called line for other connections, and to hold the secondary connecting circuit selector (if employed), connecting circuit selector and line finder in 85 their actuated positions, whereby the operator may again be placed in connection with such line, the key 705 of the connecting circuit is actuated from normal interrupting, by the opening of normal contacts 90 2 and 3 thereof, connection of the line with the repeating coil 753 and negative battery in connection therewith. The opening of contact 4 of 705 prevents the closure of a circuit for the flow of current through lamp 95 701, preventing the illumination of such lamp during the off-normal position of the key 705, and, by the opening of the normal contact and closure of the alternate contact 1 of the key 705, the ground connection to 100 the passive contacts 603 and 503, acting to short-circuit windings of relay 506 and the line lamp LL, or LL² or the lamps LL³, as the case may be, is interrupted and circuit established for the flow of current through 105 the windings of relay 506, from ground, windings of 506, normal contact 2 of ST', brush W¹⁰, engaged passive contact 503, normal contact 2 of ST², brush W¹⁵, its engaged contact 603 (if a secondary connecting circuit selector be employed), alternate contact 1 of 705, winding of 769, negative battery, to ground, which energizes the relay 506 to move its armature in a direction such as to interrupt its normal contacts and close 110 its alternate contact, which interrupts the connection to the line lamps, and the opening of normal contact 2 interrupts the then existing circuit for the flow of current through the winding of cut-off relay CO, or CO², or 115 CO³, as the case may be, which is deenergized, placing the line in condition to be used as a calling line or called line. 120

The closure of alternate contact 2 of relay 506, prior to the opening of its normal contact 2, establishes a holding circuit for the relay 510 and (if a secondary connecting circuit selector be employed) for the relay 607, whereby the relays are held in their energized position, which may be traced from 130

ground, contact 1 of 747, alternate contact 4 of 752, normal contact 3 of 750, passive contact 602, brush W¹⁴ in engagement therewith, contact 4 of ST², winding of 607 (assuming a secondary connecting circuit to be employed), passive contact 502, brush W⁹ in engagement therewith, normal contact 3 of ST', alternate contact 3 of 509, lower winding of relay 510, POR', alternate contact 2 of 506, winding of coil 511, negative battery, to ground, which holds the relays in their energized position, maintaining the secondary connecting circuit selector, connecting circuit selector, and line finder in their actuated positions as long as the key 705 remains in its off-normal position.

Should, at the time of an attempted selection of the line of a called substation, all available paths leading to the called terminals thereof be unselectable, or the line be busy, and it be desired to repeat the attempt, the operator, after actuating from normal the holding key 705 and retaining thereby the connecting circuit selector or selectors and line finder in their actuated positions by actuating from normal the key 708 of the connecting circuit and then actuating the common key 721, the district selector, local incoming selector, hundreds selector, and final selector, or such of them as were actuated, are, by the opening of the contact of 721, caused, in the manner described, to be restored. Thereafter, following the restoration of the actuated keys, the line of the calling substation is again connected to the talking strands of the connecting circuit and circuit for the flow of current through the winding of relay 754 established from ground, contact of 707, normal contact 4 of 706, contact 2 of 752, normal contact 4 of 750, normal contact 4 of RR³, contact 4 of 705, winding of relay 754, negative battery, to ground, which energizes and establishes circuits previously described causing connection of an impulse transmitter with the connecting circuit whereby, after actuation of the recording keys, the directly actuated selector switches are operated to connect with the line of the called substation.

50 (K) *Ring back keys.*

Should the calling subscriber in the meantime "hang up," the operator will actuate from normal the listening key 708 of the connecting circuit and the corresponding one of the "ring back" keys 725 to 728, inclusive, which establishes circuit for the flow of current through the winding of relay 759, from ground, positive battery, winding of 767, contact of 729 (now closed), contact 3 of 732, winding of relay 759, normal contact 2 of 758, to ground, or alternate contact 2 and left-hand winding of relay 758, negative battery to ground, which, responding by the opening of its normal contacts 1 and 2, dis-

connects the line of the calling substation from series connection with the winding of relay 751, left-hand windings of repeating coil 753 and negative battery, and by the closure of the alternate contacts 1 and 2 of 70 750, circuit is established for the flow of signaling current from grounded ringing device (not shown), alternate contact 2 of 725 (the key assumed to be actuated), alternate contact 4 of 729 (now closed), contact 2 of 75 706, alternate contact 2 of 750, normal contact 3 of 705, thence over the lower heavily drawn conductors through the connecting circuit selectors and line finder, over line conductor 102, or 202, or 302, depending 80 upon the class of the line to the substation, through the signaling apparatus thereof to ground; or, returning over line conductor 101, or 201, or 301, through the line finder, connecting circuit selector or selectors, contact 2 of 705, alternate contact 1 of 750, normal contact 1 of 706, contact 2 of 732, alternate contact 2 of 729, alternate contact 1 of 725 to ground, which actuates the substation 85 signaling apparatus. 90

Following the release of the key 725 (which is non-locking) and the response of the calling and called subscribers, conversation may proceed, and thereafter the apparatus restored to normal in the manner described. 95

(L) *Simultaneous operation of two or more listening keys.*

If the key 708 of two or more connecting 100 circuits of a secondary group be simultaneously in their off-normal position, circuits are established from ground, through the lower winding of differentially wound relay 732, contact 2 of each actuated key 708, through 105 the winding of common relay 733, negative battery to ground, and from ground, through the upper winding of 732, contact 4 of each actuated key 708, upper winding of each of the corresponding relays 755, negative battery to ground, energizing the relay 732, which, by the opening of its normal contacts, prevents the operation of the apparatus responsive to actuations from normal 110 of any of the keys from 721 to 728, inclusive, 115 of the position.

(M) *Busy condition of all connecting circuit finders switches.*

The arrangement of the circuits for relay 120 730 is such that normally its winding is short-circuited through the normal contact 1 of PON¹⁴ of each connecting circuit finder of the associated group with the result that so long as there remains closed a normal 125 contact 1 of PON¹⁴ of any connecting circuit finder of the group, the energization of the relay 730 is prevented. However, whenever all of the connecting circuit finders of the group are simultaneously out of normal 130

position, the short circuit, by the opening of the normal contact of PON^{14} of each such finder, is removed and circuit for the flow of current established from ground, winding of relay 730, alternate contact 1 of PON^{14} of each connecting circuit finder of the group, through the winding of the common coil 819, negative battery, to ground, which energizes the relay 730 and connects ground, through its contacts, to the passive contacts 501 and 601 corresponding to each minor group of the associated secondary group of connecting circuits, which prevents the selection of either of the minor groups of the associated secondary group of connecting circuits by any of the connecting circuit selectors or secondary connecting circuit selectors. Thereafter, upon the restoration to normal of any one of the connecting circuit finders of the group and the closure thereby of the normal contact 1 of PON^{14} thereof, the winding of relay 730 is again short-circuited, the relay deenergized, its contacts opened and ground connection therethrough disconnected from the contacts 501 and 601.

The circuit arrangements of the relays 714, GBC, GBC', etc., are similar and will not be described.

30 *Inter-office connections.*—Employing circuits and apparatus illustrated in Figs. 1—2—3—4—5—6—7—8—9—10—12—13—14 and 15, arranged and illustrated in Fig. 37.

In the establishment of the connection of a calling substation of a line terminating in an automatic call distributing office with a substation, as a called substation, of a line terminating in another call distributing office, the selection of the connecting circuit, connection of an impulse transmitter therewith and the operation of the impulse transmitter are accomplished in the manner substantially as described for intraoffice connections. It will be assumed that the office in which terminates the line of the substation to be called corresponds to the key C of the office group, and that the numerical designation of the substation is the same as that of the described intraoffice connection, that is, the number of the called substation is assumed to be C5346. The operator, upon observing the lighted condition of the lamp 701 and ascertaining the number of the called substation, will actuate from normal the recording keys C, 5, 3, 4 and 6 of the office, thousands, hundreds, tens and units groups respectively, whereupon the brush W^{20} of the district, office, thousands, hundreds, tens and units sections will be adjusted to connection with its eighth, tenth, fourteenth, eighth, ninth, thirteenth contact 911 respectively from normal. Thereafter, during the return to normal of the brush of the district section of the impulse transmitter, three impulses of current are trans-

mitted through the winding of motor magnet PM^3 of the district selector, and in the manner hereinbefore described, the brushes W^{22} , W^{23} , W^{24} rotated to connection with the group passive contacts 1004 and 1006 respectively, corresponding to the third row of contacts 1001 to 1003 inclusive, and the brushes W^{19} to W^{21} inclusive rotated to the position opposite to and in position to be rotated into and out of connection 75 with the associated contacts 1001 to 1003 inclusive, to which are multiply connected terminals of trunk lines leading to and terminating in office selector switches (Fig. 14), to the passive contact of which 80 are connected selective terminals of trunk lines leading to the office in which terminates the line of the called substation.

In the herein illustrated arrangement, the number of trunk lines corresponding to the third district terminating in office selector switches are multiply connected to a single row of passive contacts of a particular plurality of district selectors. Therefore, after adjustment of the brushes of the district selector to the third row, the brushes W^{19} to W^{21} inclusive are rotated step by step, responsive to automatic energizations of the motormagnet SM^3 , until the brushes W^{19} to W^{21} engage passive contacts 1001 to 1003 95 inclusive, terminals of a trunk line leading to and terminating in an office selector then idle and in normal position, whereupon the brushes come to rest and extend the connection to such trunk line, in the manner substantially as hereinbefore described.

Operation of office selector.

Following the selection of an idle office selector the initial energizing circuit of the relay RR^8 of such office selector is established, the relay energized and a holding circuit therefor established, from ground, over the previously traced path, normal contact 4 of ST^8 , brush W^{21} in connection with the passive contact 1003 multiply connected with the selected office selector, contact 2 and left-hand winding of RR^8 , negative battery to ground, which holds the relay RR^8 in its energized position so long as the relay 115 RR^8 remains energized.

Following the return to normal of the district section of the impulse transmitter, circuit for the magnet RM^3 of the office section of the impulse transmitter is established, whereby the associated brush W^{20} is released and started on its return to normal, transmitting five impulses of current through the winding of motormagnet PM^3 of the selected office selector, rotating the brushes W^{45} and W^{46} to connection with the passive contacts 1404, 1405 of the fifth row of contacts 1401 to 1403 inclusive, terminals of a minor group of trunk lines, each leading to and terminating in an interoffice in- 130

coming selector (Fig. 15, Parts 1 and 2) located in the office in which terminates the line of the called substation. The circuit of the impulses from the impulse transmitter through the motormagnet PM^s is established over the path previously traced to the brush W^{19} , and thence through the engaged contact 1001, contact 2 of SON^s , normal contact 4 of PT^s , winding of PM^s , negative battery to ground. During the transmission of the impulses through the winding of the motormagnet PM^s , the energization of relay PT^s is prevented by the presence of a short circuit around its winding, which may be traced from the right-hand contact of relay 815, and thence over the previously traced path to the brush W^{20} , contact 1002 in engagement therewith, alternate contact 1 of PON^s , contact 1 of PT^s , normal contact of SON^s , to one terminal of the winding of PT^s , the other terminal of which is connected with ground through alternate contact 2 of PON^s . After the transmission of the impulses through the winding of motormagnet PM^s , the brush of the office section of the impulse transmitter continuing its return, after passing out of connection with its fifth contact from normal, by the opening of its contact 914, the relay 815 is de-energized, its contacts interrupted, which interrupts the short circuit from around the winding of relay PT^s , whereupon circuit is established for the flow of current from ground, contact 2 of PON^s , winding of PT^s , winding of coil 1406, negative battery to ground, which energizes the relay PT^s , and assuming all of the trunk lines connected with the passive contacts of the directly selected row to be, at the time, busy, and the contact 1405 of the row now in engagement with brush W^{46} connected with ground through alternate contact of relay GBC^s of the row or minor group establishes a vibratory circuit for the flow of current through the winding of PM^s , from grounded contact 1405, brush W^{46} , contact 3 of PT^s , upper interrupter contact of PM^s , alternate contact 4 of PT^s , winding of PM^s , negative battery to ground, which responding, in the manner described, rotates the brushes W^{42} to W^{46} inclusive to the next succeeding and last row of passive contacts 1401 to 1403 inclusive, multiple terminals of trunk lines of the selected group, when, owing to the absence of ground connection with the passive contact 1405 of such row, circuit for the flow of current through the winding of PM^s , is interrupted and further actuation of the magnet prevented. Thereupon, owing to permanent ground connection with the corresponding group passive contact 1404, circuit is established for the flow of current through the winding of relay ST^s from grounded contact 1404, brush W^{45} , contact 3 of SON^s , contact 2 of PT^s , winding of relay ST^s , negative battery to ground, which energizes the relay and establishes a vibratory circuit for the flow of current through the winding of magnet SM^s , from ground, contact 2 of ST^s , interrupter contact and winding of SM^s , negative battery to ground, which responds and rotates the brushes W^{42} to W^{44} , inclusive, into connection with the first set of passive contacts 1401 to 1403, inclusive, of the row, whereupon as a result of the opening of contact 3 of SON^s , the traced energizing circuit for the relay ST^s therethrough is interrupted, and unless the engaged passive contact 1401 to 1403 inclusive be terminals of a busy trunk line, the relay will be de-energized, the vibratory circuit through SM^s interrupted and the trunk selected. If, however, as is assumed, the first trunk of the row be busy, then the multiply connected passive contact 1403 will be connected with ground, either through the normal contact 4 of ST^s of some other office selector, or through the contact 2 and lower winding of relay 1501 of the trunk. Therefore, when the brush W^{44} engages contact 1403, which occurs prior to the opening of contact 3 of SON^s , a holding circuit is established for the relay ST^s , from the grounded contact 1403, brush W^{44} , alternate contact 4 of ST^s , alternate contact 3 of RR^s , winding of relay ST^s , negative battery to ground, which holds the relay ST^s in its energized position, maintaining thereby the vibratory circuit through the winding of motormagnet SM^s , which continues to respond and rotate the brushes W^{42} to W^{44} , inclusive, step by step into and out of engagement with the sets of passive contacts 1401 to 1403, inclusive, of the row until a set connected with a trunk line then idle is engaged, when, owing to the absence of ground connection with the contact 1403, the holding circuit through the relay ST^s is interrupted, the relay de-energized, and, by the opening of its contact 2, the vibratory circuit for the magnet SM^s interrupted, preventing thereby further actuation of the magnet leaving the brushes W^{42} to W^{44} inclusive in connection with contacts 1401 to 1403 inclusive respectively, multiple terminals of the trunk line. Or should all of the trunk lines of the directly selected group be in use, the brushes will be rotated to the last row or minor group of passive contacts of the selected group, and the brushes W^{42} to W^{44} , inclusive, thereupon rotated step by step into and out of connection with the contacts of the row to the position one step beyond the last set of contacts of the row, when, by the closure of the contacts of SOR^s , the interrupter I^s is connected with the lower strand of the trunk, whereby the remaining sections of the im-

pulse transmitter are caused to be restored to normal, following which, in the manner described, the lamp 704 is caused to "flash."

Operation of inter-office incoming selectors.

5. Following the selection of an idle trunk line terminating in an interoffice incoming selector in the office in which terminates the line of the substation being called, circuit 10 for the flow of current is established from ground, winding of relay 813, contact 922 now closed, thence over the previously traced path to brush W^{43} , through contact 1402, upper winding of relay 1501, normal contact 2 of 1513, upper normal contact 1517, left hand winding of relay 1514, returning over the upper strand of the selected trunks, through normal contact 1 of 1513, contact 1401, brush W^{42} in engagement therewith, contact 1 of ST^s , contact 1001, brush W^{41} , contact 3 of 812, winding of coil 817, negative battery to ground, which energizes the relays 813, 1501 and 1514. The energization of relay 813 establishes, upon the return 25 to normal of the brush of the office section of the impulse transmitter, in the manner hereinbefore described, circuit for the magnet RM^s of the thousands section of the impulse transmitter, whereupon the brush thereof 30 starts on its return to normal.
- The energization of relay 1501, by the closure of its contact 1, short-circuits its upper winding, and by the closure of its alternate contact 2 a holding circuit is established 35 therefor from ground, normal contact 4 of ST^s , brush W^{44} , engaged passive contact 1403 of the trunk line, lower winding and alternate contact 2 of relay 1501, thence through the normal contact 2 of the relays 40 1501 of the remaining idle trunk lines of the minor group, through coil 1522, negative battery to ground, or, if the trunk be of the first minor group and all remaining trunks thereof be busy, through the winding of 45 GBC^s , winding of 1522, negative battery to ground, which holds the relay in its energized position so long as the normal contact 4 of relay ST^s remains closed.
- Responsive to the initial energization of 50 relay 1514, a circuit for the flow of current is established from ground, alternate contact 1 of 1514, normal contact 1 of PON^s , winding of slow release relay 1515, negative battery to ground, which energizes the relay 55 1515 and, by the closure of its contact 2, a holding circuit therefor is established from ground, alternate contact 1 of 1514, contact 2 and winding of 1515, negative battery to ground, which holds the relay in its energized position so long as relay 1514 remains 60 energized, and, owing to the slowness of its restoration to normal, during the deenergization of the relay 1514, responsive to impulses therethrough from the impulse transmitter.
- The closure of contact 3 of 1515 establishes circuit for the flow of current from ground, contact 3 of 1515, upper winding of differentially wound relay 1508, negative battery to ground, which, owing to the interruption of contact 1 of 1520 at this time, energizes the relay 1508, and, by the closure of its alternate contact 2, establishes circuit from ground, contact 3 of 1515, alternate contact 2 of 1508, winding of relay 1509, 70 negative battery to ground, which energizes the relay 1509, whereupon a circuit is established from ground, contact 3 of 1515, contact of GTR' , contact 2 and winding of 75 1509, negative battery to ground, which holds the relay 1509 energized so long as the contact of GTR' and contact 3 of 1515 remain closed.
- Following the selection of an interoffice 80 trunk and the return to normal of the office section of the impulse transmitter, by the closure of contact 918 of the office section, the energizing circuit for the magnet RM^s of the thousands section is established, the brush of the section restored to normal, 85 during which nine impulses of current are transmitted, through contact 915 of the thousands section, through the coil 817, whereby relay 1514, for each such closure of the contact 915 of the thousands section, is 90 deprived of current, resulting in nine deenergizations and energizations thereof. For each such deenergization of the relay 1514, a circuit is established for the flow of current through the winding of PM^s , from 95 ground, contact 3 of 1515, normal contact 3 of 1520, normal contact 2 of 1524, contact 2 of SON^s , normal contact 4 of PT^s , winding of PM^s , negative battery to ground, which responds and in the 100 manner described rotates the brushes W^{47} to W^{52} inclusive step by step to the position with the brushes W^{47} to W^{49} inclusive opposite the ninth row of passive contacts 1502 to 1504 inclusive, and the brushes W^{50} to 110 W^{52} in connection with the corresponding group contacts 1505 to 1507 inclusive.
- Responsive to the first deenergization of 115 relay 1514, as the result of the closure of contact 915 of the thousands section of the impulse transmitter, circuit is established from ground, normal contact 1 of 1514, contact 4 of 1515, winding of slow release relay 1516, negative battery to ground, which energizes 120 1516 and, by the closure of its alternate contact, places a short circuit around the winding of relay PT^s , which may be traced from ground, contact 3 of 1515, normal contact 3 of 1520, alternate contact of 1516, normal contact 2 of PT^s , normal contact 3 of SON^s , to one terminal of the winding of relay PT^s , the other terminal of which is connected, upon the first step of the brushes, responsive to the first energization of PM^s with ground, through contact 2 of 125 130

PON^o, which prevents, as long as the slow release relay 1516 remains in its energized position, the energization of relay PT^o.

During the return to normal of the brush 5 of the thousands section of the impulse transmitter, after the transmission of the impulses through its contact 915, circuit through the winding of relay 1514 is continued and the relay energized a sufficient 10 length of time to allow, by the opening of its normal contact 1, the deenergization and return to normal of relay 1516, which, by the opening of its alternate contact, interrupts the traced short circuit around the winding 15 of PT^o, whereupon the relay PT^o is energized over a circuit for the flow of current from ground, contact 2 of PON^o, winding of relay PT^o, coil 1523, negative battery to ground, which, by the opening of its normal contact 4, interrupts the previously 20 traced connection of the magnet PM^o with the contact 2 of 1514 and by the closure of its alternate contacts 3 and 4 the winding of the magnet PM^o is connected with the 25 brush W³¹. The closure of contact 1 of PT^o connects relay ST^o with brush W⁵⁰, and the closure of alternate contact 2 of PT^o establishes circuit for the flow of current from ground, alternate contact 2 of PT^o, normal 30 contact 1516, winding of relay 1517, negative battery to ground, which energizes the relay 1517, establishing a holding circuit for relay 1514 from ground, alternate contact of 1517, through right-hand winding of 1514, 35 negative battery to ground, and by the opening of its normal contact interrupts the existing circuit through the left-hand winding of 1514 and the winding of 813, whereby the relay 813 is deenergized to prevent 40 the energization of the release magnet RM^o of the hundreds section of the impulse transmitter to cause the restoration to normal of the brush of the section.

If, as is assumed, all of the trunk lines 45 connected with the sets of passive contacts 1502 to 1504 inclusive of the directly selected row, be busy, then the corresponding relay GBC^o will, as previously stated, be energized, its normal contact opened and its 50 alternate contact closed, with the result that the group contact 1505 will be disconnected from ground and the group test contact 1506 connected with ground. Therefore, following the energization of relay PT^o, circuit 55 is established for the flow of current through the winding of PM^o, from ground, alternate contact of GBC^o, multiply connected passive contact 1506, brush W⁵¹ in engagement therewith, contact 3 of PT^o, upper interrupter contact of PM^o, alternate contact 4 of 60 PT^o, winding of PM^o, negative battery to ground, which responds and rotates the brushes from the ninth to the tenth row of contacts 1502 to 1504 inclusive, multiply connected terminals of hundreds selectors of

the second and last minor group of the directly selected group, whereupon, owing to the absence of ground connection with the passive group contact 1506 of the row, circuit through the winding of magnet PM^o 70 is interrupted, and its further actuation prevented. Upon the engagement of brush W⁵⁰ with the group contact 1505 of the tenth row, owing to the permanent ground connection therewith, circuit is established 75 from grounded contact 1505, brush W⁵⁰ in engagement therewith, contact 1 of SON^o, contact 1 of PT^o, winding of relay ST^o, negative battery to ground, which energizes the relay ST^o and establishes a vibratory 80 circuit through the winding of magnet SM^o from ground, contact 2 of ST^o, interrupter contact and winding of SM^o, negative battery, to ground, which responds and rotates the brushes W⁴⁷, W⁴⁸, W⁴⁹ into engagement 85 with their corresponding first set of passive contacts 1502 to 1504, inclusive, multiply connected with a trunk line of the row or minor group which leads to and terminates in a hundreds selector. 90

Should, as is assumed, the trunk connected with the first set of contacts 1502 to 1504 inclusive be busy, then prior to the opening of contact 1 of SON^o, by the connection of brush W⁴⁹ with the contact 1504, a holding 95 circuit is established for the relay ST^o from ground, normal contact 3 of the relay ST^o, brush W⁴⁹, multiply connected contact 1504 of some other interoffice incoming selector, or from ground, normal contact 4 of relay 100 ST^o, brush W²¹, multiply connected passive contact 1103 of a local incoming selector (Fig. 11), or from ground, normal contact 4 of relay ST¹², brush W⁷⁸ and passive contact 1919 of a manual incoming trunk 105 selector (Fig. 19, Part 2), to contact 1504, brush W⁴⁹ in engagement therewith, alternate contact 3 of ST^o, alternate contact 1 of of 1515, winding of ST^o, negative battery to ground, which maintains the relay in its 110 energized position and the vibratory circuit through SM^o closed, whereby the brushes W⁴⁷ to W⁴⁹ inclusive are rotated step by step into and out of engagement with their associated sets of passive contacts 1502 to 115 1504, inclusive, until the set connected with an idle hundreds selector is engaged, whereupon, owing to the absence of ground connection with the contact 1504, the holding circuit through the relay ST^o is interrupted, 120 the relay deenergized and, by the opening of its contact 2, the vibratory circuit through the magnet SM^o interrupted, preventing its further actuation, thereby leaving the brushes W⁴⁷ to W⁴⁹, inclusive, in connection 125 with their corresponding contacts 1502 to 1504, inclusive, of such idle trunk line.

Upon the movement of the brushes W⁴⁷ to W⁴⁹, inclusive, into engagement with their associated first set of passive contacts 1502 130

to 1504, inclusive, by the closure of alternate contact 3 of SON^o a short circuit is placed around the winding of PT^o, whereby the relay is deenergized, and, by the opening of its contact 3, alternate contact 4, the winding of PM^o is disconnected from brush W⁵¹.

During the energization of relay ST^o, a holding circuit is established for relay 1517
10 from ground, alternate contact 4 of ST^o, normal contact 4 of 1513, normal contact of 1516, winding of 1517, negative battery, to ground, which maintains the relay energized during the movement of the brushes W⁴⁷ to 15 W⁴⁹, inclusive, until the hundreds selector is selected, whereby the establishment of circuit for the relay 813 is prevented.

Following the selection of an idle hundreds selector and the closure of normal contact 3 of relay ST^o, ground is connected with the multiply connected test passive contact 1504 of the selected trunk line, which prevents the selection of such hundreds selector by any other interoffice incoming selector, 20 local incoming selector or manual incoming trunk selector, to the passive contacts of which the trunk line is connected.

Operation of hundreds selector in the establishment of an inter-office connection.

Also responsive to the deenergization of relay ST^o, by the interruption of its alternate contact 4 the traced holding circuit through the relay 1517 is interrupted, which deenergizes, interrupting the holding circuit through the relay 1514, and by the closure of its normal contact reestablishes the previously traced energizing circuit 35 through the winding of relay 813 and the left-hand winding of relay 1514, whereby the relay 1514 is held in its energized position and the relay 813 energized, which, by the closure of the contact of 813, establishes 40 circuit through contact 918 of the thousands section for the magnet RM³ of the hundreds section of the impulse transmitter, which, in the manner described, is energized, and the associated brush started on 45 its return to normal, causing three closures and interruptions of the contact 915 of the hundreds section, and responsive thereto, three deenergizations and energizations of the relay 1514, resulting for each such de- 50 energization, in the transmission of an impulse of current through the magnet PM^o of the selected hundreds selector, from ground, contact 3 of 1515, normal contact 2 of 1514, contact 1 of 1508, alternate contact 60 1 of 1509, contact 1 of ST^o, brush W⁴⁷, its engaged contact 1502, thence over the previously traced path through the winding of PM^o, negative battery, to ground, whereby the brushes W⁵¹ to W⁵⁵, inclusive, are rotated to the third row of contacts 65 1201 to

1203, inclusive multiply connected terminals of final selector switches of the first minor group of the second hundreds group of the fifth thousands groups, to a set of the passive contacts of which are multiply connected called terminals of the line of the called substation.

The first deenergization of relay 1514, responsive to the first closure of contact 915 of the hundreds section of the impulse transmitter, establishes the previously traced energizing circuit for the relay 1516, which responds, whereupon circuit is established for the flow of current from ground, contact 3 of 1515, alternate contact of 1516, 70 normal contact 4 of 1513, alternate contact 3 of 1508, alternate contact 3 of 1509, normal contact 4 of ST^o, brush W⁴⁸, its engaged passive contact 1503, normal contact 1 of PON^o, right-hand winding of RR^o, negative battery, to ground, which energizes the relay RR^o and establishes a holding circuit therefor, from ground, normal contact 3 of ST^o, brush W⁴⁹, its engaged contact 1504, 80 contact 2 and left-hand winding of RR^o, negative battery to ground, which holds the relay RR^o energized so long as the relay ST^o remains deenergized.

Thereafter, during the return to normal of the brush of the hundreds section of the impulse transmitter, following the closures and interruptions of its contact 915, circuit for the relays 813 and 1514 is maintained a length of time sufficient to cause, in the manner described, the deenergization of the relay 1516, which, by the opening of its alternate contact removes the then existing short circuit from around the winding of relay PT^o, which may be traced from ground, contact 3 of 1515, normal contact 3 of 1520, alternate contact of 1516, normal contact 4 of 1513, alternate contact 3 of 1508, alternate contact 3 of 1509, normal contact 4 of ST^o, brush W⁴⁸, its engaged contact 1503, alternate contact 1 of PON^o, normal contact 1 of PT^o, normal contact 1 of SON^o to one terminal of winding of PT^o, whereupon the relay PT^o is energized and the brushes W⁴⁷ to W⁴⁹ inclusive moved to connection with a set of passive contacts multiply connected with an idle final selector of the directly selected group, in the manner previously described. During the selection of a minor group, by the closure of alternate contact 1 of PT^o an energizing 100 circuit for the relay 1517 is established, from ground, alternate contact 1 of PT^o, alternate contact 1 of PON^o, passive contact 1503 and brush W⁴⁸ in engagement therewith, normal contact 4 of ST^o, alternate 105 contact 3 of 1509, alternate contact 3 of 1508, normal contact 4 of 1513, normal contact of 1516, winding of 1517, which, in the manner described, interrupts the circuit 110 through the relay 813, the left-hand wind- 115 120 125 130

ing of relay 1514, and establishes the previously traced holding circuit through the right-hand winding of 1514.

Thereafter; during the movement of the 5 brushes of the hundreds selector to selective connection with the terminals of an idle selector switch of the selected row or minor group, a circuit is established from ground, alternate contact 3 of ST^e, thence 10 over the previously traced path, through the winding of relay 1517, whereby, during the automatic selecting operation of the hundreds selector, the energization of relay 813 is prevented.

15 *Operation of final selector in the establishment of an inter-office connection.*

Following the selection of an idle final selector, by the opening of contact 3 of ST^e 20 the circuit through relay 1517 is interrupted, the relay deenergized, circuit for the flow of current through the right-hand winding of 1514 interrupted and the previously traced circuit through the winding of relay 813 and 25 the left-hand winding of 1514 again established, the relays energized, which, by the closure of the contact of relay 813, establishes the previously described energizing circuit for the magnet RM³ of the tens section of the impulse transmitter, responsive to 30 which the brush of the tens section of the impulse transmitter restores to normal, causing four closures and interruptions of its contact 915, resulting in four deenergizations 35 and energizations of the relay 1514, and the transmission, responsive thereto, of four impulses of current through the winding of motormagnet PM^e of the final selector over the previously traced path to the 40 brush W³¹, its engaged contact 1201, and thence over the path traced in the operation of establishing an intra-office connection, whereby the brushes W³⁶ to W⁴¹, inclusive, are rotated to the fourth row of their 45 passive contacts.

Responsive to the first deenergization of relay 1514 as a result of the first closure of the contact 915 of the tens section of the impulse transmitter, the previously traced energizing circuit through the relay 1516 is 50 established, following which, by the closure of its alternate contact, circuit may be traced through the right-hand winding of relay RR^e, which is energized, and by the 55 closure of its alternate contact 2 the described holding circuit therefor, through its left-hand winding, may be traced.

Upon the first step of the brushes of the final selector from normal by the closure of 60 lower alternate contact of PON^e, a short circuit is placed around the winding of relay PT^e, which may be traced from ground, thence over the previously traced path to normal contact 3 of ST^e (Fig. 12), brush 65 W³², its engaged contact 1202, lower alter-

nate contact of PON^e, thence, as described, to one terminal of the winding of PT^e, the opposite terminal of which is connected to ground through the upper alternate contact of PON^e, which prevents the energization 70 of relay PT^e.

Following the closures and interruptions of contact 915 of the tens section of the impulse transmitter, circuit is again established through the relays 813 and 1514 a length of 75 time sufficient to cause the deenergization of relay 1516 which, by the opening of its alternate contact, interrupts the short circuit from around the winding of PT^e, whereby the relay PT^e is energized, and by the closure of its alternate contact 4 establishes an energizing circuit for the relay 1517, which may be traced from ground, upper alternate contact of PON^e, alternate contact 3 of RR^e, lower normal contact 2 of ST^e, 85 alternate contact 4 of PT^e, normal contact 4 of 1307, normal contact 4 of BFR, lower alternate contact of PON^e, contact 1202, brush W³² in engagement therewith, normal contact 3 of ST^e, contact 1503, brush 90 W⁴⁸ in engagement therewith, normal contact 4 of ST^e, thence over the previously traced path through the winding of 1517, negative battery to ground, resulting in the interruption, as described, of circuit through 95 relay 813 and left-hand winding of 1514, and in the closure of a holding circuit through the right-hand winding of 1514, preventing thereby the closure of circuit for the magnet RM³ of the units section of the 100 impulse transmitter. Thereafter, upon the energization of the relay ST^e, by the opening of its lower normal contact 2, circuit through the relay 1517 is interrupted, the relay deenergized, its alternate contact 105 opened and its normal contact closed, resulting in the interruption of circuit for the flow of current through the right-hand winding of relay 1514 and the closure of the previously traced energizing circuit through 110 the winding of relay 813 and the left-hand winding of relay 1514, which, by the closure of the contact of 813, establishes, as described, the energizing circuit for the magnet RM³ of the units section of the impulse 115 transmitter, whereby the brush of the section returns to normal, causing six closures and interruptions of its contact 915, resulting in six deenergizations and energizations of the relay 1514 and the transmission of six 120 impulses of current over a circuit from ground, contact 3 of 1515, thence over the previously traced path to normal contact 3 of 1307, normal contact 3 of BFR, contact 1 of ST^e, normal contact of XT, winding of 125 SM^e. The magnet SM^e responding in the manner described, rotates the brushes W³⁶ to W⁴¹, inclusive, into engagement with their sixth set of passive contacts 1301 to 1304 inclusive respectively.

Responsive to the first deenergization of magnet 1514, as a result of the first closure of contact 915 of the units section, during the return of its brush to normal, the previously traced energizing circuit for the magnet 1516 is established, which closes its alternate contact and establishes, upon the first step of the brushes W^{26} to W^{29} inclusive into engagement with their first set of passive contacts of the selected row, a short circuit around the winding of relay 1308, which may be traced from ground, contact 3 of 1515, thence through alternate contact of 1516 to lower alternate contact of PON^6 , normal contact 4 of BFR, normal contact 4 of 1307, alternate contact 4 of $S1^6$, to one terminal of the winding of 1308, the opposite terminal of which is connected with ground through contact of SON^6 , which prevents, during the rotation of the brushes W^{26} to W^{29} , inclusive, into and out of engagement with their passive contacts, the energization of the relay 1308.

During the return to normal of the brush 25 of the units section of the impulse transmitter, following the last interruption of its contact 915, circuit through the relay 813 and the left-hand winding of relay 1514, is again maintained a length of time sufficient 30 to cause the return to normal of the relay 1516, whereupon the short circuit around the winding of relay 1308 is removed and the relay energized over a circuit from ground, contact of SON^6 , normal contact 1 of BFR, 35 normal contact 2 of 1307, winding of 1308, winding of coil 1312, negative battery, to ground, following which, by the closure of contact of 1308, the circuit, as described, is established for the relay 1309, which 40 responds and, by the closure of its contact 1, establishes the energizing circuit for the relay 1307, which responds, establishing, by the closure of its alternate contact 2, its holding circuit, whereupon circuit is established 45 for the flow of current, from ground, normal contact of relay LR, or LR^2 , or LR^3 , normal contact 3 of CO, or CO^2 or CO^3 , as the case may be, contact 1304, brush W^{29} in engagement therewith, contact 3 of 1309, 50 alternate contact 3 of 1307, passive contact 1201, brush W^{21} in engagement therewith, contact 1 of ST^6 , passive contact 1502, brush W^{27} in engagement therewith, contact 1 of ST^6 , alternate contact 1 of 1509, alternate 55 contact 1 of 1508, alternate contact 2 of 1514, contact 3 of PON^6 , normal contact 2 and winding of 1520, negative battery, to ground, which energizes the relay 1520 establishing thereby a holding circuit from 60 ground, contact 2 of PON^6 , winding of 1520, negative battery, to ground, which maintains the relay in its energized position. The closure of alternate contact 3 of 1520 establishes circuit for the flow of current from

ground, alternate contact 3 of 1515, alternate 65 contact 3 of 1520, normal contact 3 and winding of relay 1513, negative battery, to ground, which energizes relay 1513 and establishes a holding circuit therefor from ground, contact 2 of PON^6 , alternate contact 3 and winding of 1513, negative battery, to ground, which holds the relay in its energized position as long as the contact 2 of PON^6 remains closed. Simultaneous therewith, by the opening of the normal and closure of the alternate contacts 1 and 2 of 1513, the left-hand winding of 1514 is disconnected from the trunk line leading to the office in which terminates the line of the calling substation, and the left-hand windings of the 80 repeating coil 1510, in which is included the windings of relay 1511, bridging the condenser serially connected with the windings of 85 1510, connected thereto.

By the opening of contact 4 of 1513, the 85 winding of relay 1517 is disconnected from the lower talking strands of the trunk lines and is not again connected therewith during the existence of the connection.

Responsive to the connection of relay 1511 90 with the trunk line, circuit is established which may be traced, prior to the return to normal of the brush of the units section of the impulse transmitter, from ground, winding of relay 813, contact 922, contact 4 of 95 812, brush W^{23} , its engaged contact 805, normal contact 3 of 757, thence over the previously traced path, through alternate contact 2 of 1513, lower left-hand winding of repeating coil 1510, windings of 1511, upper 100 left-hand winding of repeating coil 1510, thence returning over the upper heavily drawn conductor, normal contact 2 of 757, alternate contact 2 of 756, contact 804, brush W^{22} in engagement therewith, contact 3 of 105 812, winding of coil 817, negative battery to ground, or during the movement of the brush of the units section between positions 4 and 2 inclusive, and the closure of contact 921 thereof, owing to the deenergization of relay 110 756, the circuit may be traced through normal contact 2 of 757, normal contact 2 of 756, winding of coil 764, contact 3 of RR^3 , brush W^{24} , to its engaged grounded contact 1006.

Responsive to the deenergization of relay 756, following the engagement of brush, W^{22} of the units section during its restoration with its fourth contact from normal, the described energizing circuit of relay 747 120 is established, following which the energizing circuit of relay 760 is established in multiple with the polarized relay 506, which may be traced, for the relay 760, from grounded contact 1006, brush W^{24} in 125 engagement therewith, left-hand winding of 760, alternate contact 2 of 747, winding of coil 749, positive battery, to ground,

whereupon, by the closure of its alternate contact 3, the relay is locked in its energized position over a circuit including contact 2 of RR³.

5   Responsive to the movement of the brush of the units section from connection with its second contact from normal, and as a result the energization of 756, the traced energizing circuit for the relay 757 is established, which responds and by the closure of its alternate contacts 2 and 3 connects the right-hand windings of the repeating coil and relay 746 in circuit with the relay 1511, thereby establishing circuit 10 for the flow of current from ground, upper right-hand winding of coil 753, normal contact 1 of 709, alternate contact 2 of 757, thence over the upper heavily drawn conductors through the selected trunk circuits, 15 alternate contact 1 of 1513, upper left-hand winding of repeating coil 1510, windings of relay 1511, lower left-hand winding of coil 1510, alternate contact 2 of 1513, thence over the lower heavily drawn conductors of 20 the selected trunk circuits, through alternate contact 3 of 757, windings of 746, lower right-hand winding of coil 753, negative battery, to ground; whereby, the relay 1511 is held in its energized position, but, owing 25 to the inclusion of the high resistance right-hand winding of 1511, the relay 746 is not actuated.

Following the energization of relay 1511, in response to the establishment of the 30 traced circuits for the flow of current through its windings, circuit is established for the flow of current through the lower winding of relay 1508 from ground, contact of 1511, contact 1 of 1520, lower winding 35 of 1508, negative battery, to ground, which deenergizes the relay and establishes circuit for the flow of signaling current of the proper characteristic from ground, through the signaling device (not shown) multiply 40 connected with the contact 1507, corresponding to the thousand line group in which is included the called terminals of the line of the called substation, brush W⁵² in engagement therewith, winding of relay 45 GTR', normal contact 3 of 1508, alternate contact 3 of 1509, normal contact 4 of ST³, brush W⁴⁸, its engaged contact 1503, thence over the lower heavily drawn conductors 50 through the signaling apparatus of the 55 called substation to ground, or through the signaling apparatus of the substation to the upper heavily drawn conductor, and returning thereover to passive contact 1502, brush W⁴⁷ in engagement therewith, normal contact 1 of ST³, alternate contact 1 of 60 1509, normal contact 2 of 1508, contact 3 of 1515, to ground.

Immediately following the response of the 65 called substation, by the opening of contact GTR', the described holding circuit

through relay 1509 is interrupted, whereupon the relay 1509 is deenergized and, by the closure of its normal contacts 1 and 3, connects the right-hand windings of repeating coil 1510 with the line of the called substation, establishing circuit from ground, upper right-hand winding of 1510, normal contact 1 of 1509, normal contact 1 of ST³, brush W⁴⁷, its engaged contact 1502, thence over the upper heavily drawn conductors to 70 and through the substation, returning over the lower heavily drawn conductors to contact 1503, brush W⁴⁸ in engagement therewith, normal contact 4 of ST³, normal contact 3 of 1509, alternate contact 4 of 1513, 75 winding of 1512, lower winding of 1510, negative battery, to ground, which energizes the relay 1512, and, by the closure of its contact, short circuits the right-hand high resistance winding of relay 1511, 80 whereupon the flow of current through the relay 746 over the interoffice trunk is increased to an extent sufficient to cause the opening of its normal and closure of its alternate contact, establishing thereby the 85 previously described circuit for the flow of current through the left-hand winding of 758, which responds and by the opening of its normal and closure of its alternate contact 3, the flow of current through the lamp 90 703 is interrupted, the lamp extinguished and the described holding circuit through the right-hand winding of 758 is, as described, established, thus establishing the 95 talking connection between the calling and 100 called substation and conversation may proceed.

Restoration of inter-office connection.

After completing the conversation, when 105 the called subscriber "hangs up" circuit for the flow of current through the winding of relay 1512 is interrupted, the relay deenergized, its contact opened and thereby the short circuit removed from around the right-hand high resistance winding of 1511, which 110 decreases the flow of current through relay 746 to an extent sufficient to cause the interruption of its alternate and the closure of its normal contact; whereupon the described circuit 115 for the flow of current through lamp 704 is established and its illumination effected.

When the calling subscriber "hangs up," 120 relay 751 is, as described, deenergized and the lamp 702 illuminated, whereupon the operator may cause the restoration of the apparatus by actuating from normal the proper one of the described disconnect keys, and cause, in the manner described, the restoration of the secondary connecting circuit 125 selector, (if such be employed), connecting circuit selector, line finder and district selector.

Responsive to the interruption of normal 130 contact 4 of ST³ as the result of the estab-

lishment of the restoring circuits of the district selector, the holding circuit through the left-hand winding of relay RR^s is interrupted, the relay deenergized, establishing circuit for the flow of current from ground, contact 2 of PON^s, normal contact 3 of RR^s, winding of ST^s, negative battery, to ground, which energizes the relay ST^s and by the closure of its contact 2 establishes 5 the vibratory circuit through the winding of magnet SM^s, which responds and rotates the brushes W⁴² to W⁴⁴ inclusive step by step into and out of engagement with the remaining sets of contacts 1401 to 1403, inclusive, of the row until the brushes are brought to the position two steps beyond the last set of contacts 1401 to 1403 inclusive, when the brushes W⁴⁵, W⁴⁶ are restored to normal and the brushes W⁴² to W⁴⁴, inclusive, to the position above normal, whereupon the alternate contacts of PON^s are interrupted, and simultaneously therewith the brushes W⁴² to W⁴⁴ are restored to normal. Upon the interruption of contact 2 10 of PON^s, the restoring energizing circuit for the relay ST^s is interrupted, the relay deenergized and the vibratory circuit for magnet SM^s, by the opening of contact 2 of ST^s, interrupted, preventing thereby its 15 further actuation. As described, when the brushes W⁴² to W⁴⁴ inclusive, reach their normal position, the alternate contact of SON^s is interrupted and its normal contacts closed, and the office selector placed in condition to be utilized in the establishment 20 of another connection.

The energization of relay ST^s, responsive to the establishment of the restoring circuits of the district selector by the opening of its contacts 1 and 3, interrupts circuit for the flow of current through the windings of relay 1511, which deenergizes and, by the opening of its contact, interrupts the holding circuit of the slow release relay 1515, which deenergizes and establishes circuit 25 for the flow of current from ground, alternate contact 2 of PON^s, normal contact 1 of 1515, winding of ST^s, negative battery to ground, which energizes the relay ST^s, establishes the previously traced vibratory 30 circuit through the winding magnet SM^s, which responds and rotates the brushes W⁴⁷ to W⁴⁹ inclusive step by step until they are brought to the position two steps beyond the last set of passive contacts 1502 to 1504, inclusive, of the row, whereupon the brushes W⁵⁰ to W⁵² are rotated to normal position 35 and the brushes W⁴⁷ to W⁴⁹ to the position above normal, when, by the opening of the alternate contact 2 of PON^s, the described holding circuits through the windings of relays 1513 and 1520 are interrupted and the relays deenergized.

The opening of the alternate and closure 40 of the normal contacts of SON^s, when the

brushes of the interoffice selector reach normal position, places the switch in a condition to be, upon selection of its associated interoffice trunk, actuated to establish some other connection. 70

The energization of relay ST^s, responsive to the establishment of the restoring circuits of the interoffice selector, by the opening of its normal contact 3, interrupts the holding circuit through the left-hand winding 75 of relay RR^s which deenergizes and establishes the previously described circuits, whereby the hundreds selector is restored and placed in condition to be subsequently employed in establishing another connection. 80

Likewise, responsive to the interruption of normal contact 4 of ST^s, the relay RR^s is deenergized and the final selector restored. 85

Re-ringing a called subscriber in an inter-office connection.

Should, during the existence of an inter-office connection, it be desired to "re-ring" 90 the called substation, the operator will actuate the key 709, which, by the interruption of its normal contact 1, disconnects ground, through the upper right-hand winding of repeating coil 753, from series connection 95 with the windings of relay 1511, and connects, in lieu thereof, ground through the contact of relay 735. Also, by the closure of alternate contact 4 of 709, a vibratory circuit is established for the relay 735 from 100 ground, normal contact 2 of 760, alternate contact 4 of 709, winding of 735, interrupter I^s, negative battery, to ground, which responding by the opening and closing of its contact, circuit for the flow of current 105 through the windings of relay 1511 is interrupted and closed each time the brushes of I^s establish and interrupt connection with their live segments; whereby the relay is accordingly deenergized and energized, its 110 contact opened and closed, which interrupts and closes circuit for the flow of current through the lower winding of the differentially wound relay 1508, whereby the relay 1508 is energized and deenergized responsive 115 to each closure and interruption of the brushes of I^s with their segments.

Responsive to the first energization of 1508, the previously traced energizing circuit for the relay 1509 is established, whereupon, by the closure of its contact 2, the described holding circuit therefor is established, preventing its deenergization responsive to subsequent deenergizations of relay 1508. 125

As the actuation from normal of key 709 need be only momentary, the operator immediately releases same, whereupon, by the opening of its alternate and closure of its normal contact 1, ground connection through 130

the contact of 735 with the trunk line is interrupted and circuit again established for the steady flow of current through the upper right-hand winding of 753 and the relay 5 1511, whereby the contact of 1511 is held closed and circuit established for the steady flow of current through the lower winding of 1508, which prevents its energization and, in the manner described, establishes circuit 10 for the flow of signaling current through the winding of relay GTR' over the line and through the signaling apparatus of the called substation. Thereafter, upon the response of the called party, the relay GTR' 15 is actuated, its contact opened and the holding circuit of the relay 1509 interrupted, which deenergizes and reestablishes the conversational circuit.

20 *Connections from automatic call distributing offices to manual offices*

employing circuits and apparatus illustrated in Figs. 1, 2, 3, 4, 5, 6, 7, 8, 9, 10, 14, 16, 17, 18, arranged as indicated in Fig. 37. 25 In the establishment of a connection of a calling substation of a line terminating in an automatic call distributing office with the line of a called substation terminating in a manual office, the selection of a connecting circuit, the connection of an impulse transmitter therewith, the operation of the impulse transmitter, and the operation of the district and office selectors to select an idle trunk line, terminating in the manual 30 office in which terminates the line of the called substation, is accomplished in substantially the same manner as described for interoffice connections.

In the description following, it is assumed that the office in which terminates the line of the manual substation to be called, corresponds to the recording key "F" of the office group, and that the numerical number of the substation is the same as hereinbefore described in the establishment of intraoffice and interoffice connections. Therefore, the operator, after ascertaining the number of the called substation, actuates from normal the recording keys "F" 45 5, 3, 4 and 6 of the office, thousands, hundreds, tens and units group respectively, whereupon the brush $W^{29'}$ of the district office, thousands, hundreds, tens and units section is adjusted to connection with its 50 twelfth, sixteenth, fourteenth, eighth, ninth and thirteenth passive contact 911 respectively from normal.

Thereafter, responsive to closures and interruptions of the contact 915 of the district section of the impulse transmitter, seven impulses of current will be transmitted through the winding of magnet PM^8 , and the brushes of the district selector, in the manner described, adjusted to connection with the selective terminals of an idle

office selector switch, to the passive contacts of which are multiply connected trunk lines leading to the offices of the district, included in which are the trunk lines leading to and terminating in the office "F". 70

Following the selection of an idle office selector, responsive to the closures and interruptions of contact 915 of the office section of the impulse transmitter, eleven impulses of current are transmitted through 75 the magnet PM^8 , causing, in the manner described, the selection of an idle trunk line leading to and terminating in a manually actuated plug switch in the office "F", whereupon circuit is established for the flow 80 of current from ground, winding of relay 813, contact 922, contact 4 of 812, brush $W^{23'}$, its engaged passive contact 805, thence over the previously traced path through brush W^{42} , its engaged contact 1402, upper 85 winding of relay 1601, normal contact 2 of 1625, lower left-hand winding of coil 1609, windings of relay 1618, upper left-hand winding of coil 1609, normal contact 1 of 1625, passive contact 1401 in engagement 90 with brush W^{42} , thence over the previously traced path, through contact 804 and brush $W^{22'}$ in engagement therewith, contact 3 of 812, winding of coil 817, negative battery, to ground, whereby the relay 1618 is actuated and its contact closed, but owing to the high resistance of the left-hand winding of 1618, the relay 813 is not energized sufficiently to cause the closure of its contact.

Responsive to the closure of the contact of 100 1618, circuit is established for the flow of current from ground, contact of 1618, normal contact of 1624, normal contact 2 of 1616, winding of relay 1629, negative battery, to ground, which energizes the relay 105 1629 and, by the opening of its normal contact, disconnects ground from the multiply connected passive contacts 1710 of the cord finders of the group, whereby the trunk line is rendered selectable by such cord finders. 110

The closure of the alternate contact of 115 1629 establishes the circuit for the relay GBC^{10} of the cord finder group, which is energized, its normal contact opened and its alternate contact closed, whereby the multiply connected group test passive contacts 1709 of the cord finders of the group are disconnected from ground, rendering the trunks of the corresponding group selectable by the cord finders. 120

The closure of alternate contact of GBC^{10} establishes a starting circuit for the allotted cord finder from ground, alternate contact of GBC^{10} , normal contact of relay T^4 , brush W^{53} , its engaged contact 1701, a terminal of an idle cord finder, normal contact of PON^{10} , winding of PT^{10} , negative battery to ground, which energizes the relay PT^{10} , whereupon, a vibratory circuit is established for the motormagnet PM^{10} from ground, 130

- lower alternate contact of PT^{10} , interrupter contact and winding of PM^{10} , negative battery to ground, which responds and rotates the brushes W^{61} to W^{66} inclusive step by 5 step until the brush W^{61} engages the group test contact 1709 corresponding to the actuated relay GBC^{10} , when, as a result of the absence of ground connection with the contact 1709, the holding circuit for the relay 10 PT^{10} , through its upper contact, is interrupted, the relay deenergized, and, by the opening of its lower alternate contact, the circuit through the magnet PM^{10} is interrupted and its further actuation prevented. 15
- 15 Following the deenergization of PT^{10} , circuit is established for the flow of current from ground, normal contact of PT^{10} , alternate contact of PON^{10} , contact of SON^{10} , winding of ST^{10} , negative battery to ground, 20 which energizes the relay ST^{10} and, by the closure of its contact 2, establishes a vibratory circuit for the motor magnet SN^{10} , which responds and rotates the brushes W^{62} to W^{68} , inclusive, into connection with the 25 first set of passive contacts 1710 to 1713 inclusive respectively, of the row, corresponding to the group test contact 1709 engaged by the brush W^{61} , whereupon, by the opening of contact SON^{10} , the traced energizing circuit through the relay ST^{10} is interrupted, and unless the trunk line multiply connected with the engaged contacts 30 1710 to 1713 be busy, the relay ST^{10} will be deenergized, interrupt the vibratory circuit 35 through SM^{10} , and prevent thereby further rotation of the brushes in their selecting operation.

Assuming, however, the trunk sought to be some other than the one connected with 40 the first engaged set of contacts 1710 to 1713, inclusive, owing to the connection of ground with the passive contact 1710, a holding circuit for the relay ST^{10} is, upon engagement of brush W^{62} therewith, prior to 45 the opening of contact SON^{10} , established from ground, normal contact of relay 1629, multiply connected passive contact 1710, brush W^{62} , normal contact of RR^{10} , winding of ST^{10} , negative battery to ground, where- 50 by, so long as the brush W^{62} passes into and out of engagement with its associated passive contacts 1710 of the row, which are connected with ground, the relay ST^{10} is held in its energized position, the vibratory 55 circuit through the winding of magnet SM^{10} maintained, and the rotation of the brushes continued.

When the brush W^{62} engages a contact 60 1710 multiply connected with the normal contact of an energized relay 1629, the holding circuit for relay ST^{10} is interrupted, the relay deenergized and, by the opening of its contact 2, the circuit through the winding of motor magnet SM^{10} is interrupted, where- 65 by its further actuation is prevented, and

the brushes W^{62} to W^{66} , inclusive, left in connection with the desired trunk line.

Responsive to the deenergization of ST^{10} by the closure of its normal contact 1, ground is connected through brush W^{62} 70 with the contact 1710, which prevents, pending the deenergization of the corresponding relay 1629, the selection of the trunk line by any other cord finder.

Following the deenergization of relay 75 ST^{10} , circuit is established from ground, winding of 1626, normal contact 4 of 1617, contact 4 of 1624, multiply connected passive contact 1711, brush W^{63} in engagement therewith, contact 3 of ST^{10} , winding of relay RC^{10} , negative battery to ground, which energizes the relays 1626 and RC^{10} , whereupon circuit is established for the flow of current from ground, contact 3 of 1626, lower winding of relay 1616, negative battery to ground, which energizes the relay 80 1616 and, by the opening of its normal contact 2, the traced circuit for the relay 1629 is interrupted, the relay deenergized, and, by the opening of its alternate contact, circuit for the relay GBC^{10} is interrupted, which deenergizes, interrupting, by the opening of its alternate contact, the starting circuit therethrough for the cord finders, and prevents, by the closure of its normal 85 contact, pending the selection of another trunk line of the corresponding group, the selection of the finder group by a cord finder. The closure of normal contact of 1629 connects ground with the corresponding passive contacts 1710 of each cord finder of the group, which prevents the selection of the trunk line by a cord finder.

By the closure of alternate contact 2 of 90 relay 1616, circuit is established for the flow of current from ground, contact of 1618, contact 1 of 1624, alternate contact 2 and upper winding of 1616, and in multiple therewith through the right-hand winding of differentially wound relay 1615, negative 95 battery to ground, which holds the relay 1616 energized and energizes the relay 1615, whereupon circuit is established for the flow of current from ground, alternate contact 3 of 1616, contact 2 of 1615, upper winding 100 1620, negative battery to ground, which energizes the relay 1620. Also, following the energization of relay 1616, circuit is established for the flow of current from ground, alternate contact 3 of 1616 normal 105 contact 1 of 1622, normal contact 1 of 1617, contact 1 of 1626; winding of 1625, negative battery to ground, which energizes the relay 1625, interrupting, by the opening of its normal contacts 1 and 2, circuit for the flow 110 of current through the windings of relay 1618, which is deenergized and its contact opened.

The closure of contact 3 of relay 1625 establishes a holding circuit therefor from 115 130

ground, alternate contact 3 of 1616, normal contact 1 of 1622, normal contact 1 of 1617, contact 3 and winding of 1625, negative battery to ground, which holds the relay in its energized position and permits the energization of relay 1617, following the deenergization of the relay 1626, as will be hereinafter described.

Referring to relay RC^{10} , in response to its energization in series with 1626, circuit is established for the flow of current from ground, normal contact of PT^{10} , alternate contact of PON^{10} , alternate contact 1 of RC^{10} , winding of RR^{10} , negative battery to ground, which energizes the relay RR^{10} , whereupon a holding circuit is established therefor from ground, normal contact 1 of PT^{10} , alternate contact of PON^{10} , contact 2 and winding RR^{10} , negative battery to ground, which maintains the relay in its energized position so long as the alternate contact of PON^{10} remains closed.

The closure of alternate contact 2 of RC^{10} establishes circuit for the flow of current from ground, alternate contact 2 of RC^{10} , brush W^{67} , first passive contact 1715, winding of 1717, first passive contact 1714, brush W^{66} of the decimal distributor, winding of coil 1722, negative battery to ground, which energizes the relay 1717, whereupon circuit is established through its lower alternate contact for the flow of current, which energizes the slow release relay 1718, and, by the closure of upper alternate contact of 1717, circuit is established for the flow of current from ground, upper alternate contact of 1717, normal contact of slow release relay 1719, winding of motormagnet MM^{12} , negative battery to ground, whereby the magnet is energized and the brushes W^{66} to W^{68} inclusive rotated from connection with their first or normal set of contacts 1714 to 1717, inclusive, respectively, into connection with their second set of contacts.

Following the energization of relays 1625, RC^{10} and 1718, as described, circuit is established from ground, winding of relay 813, contact 922 (now closed), thence to brush W^{23} , over the previously traced path, 50 through the alternate contact 2 of 1625, normal contact 3 of 1617, passive contact 1712, brush W^{64} in engagement therewith, contact 3 of RR^{10} , contact 4 of RC^{10} , alternate contact 1 of 1718, winding 1717, alternate 55 contact 2 of 1718, brush W^{65} , engaged passive contact 1713, normal contact 2 of 1617, alternate contact 1 of 1625, thence over the previously traced path to brush W^{22} , contact 3 of 812, winding of coil 817, negative 60 battery to ground, whereby the relays 813 and 1601 are energized, and as this circuit is established prior to the movement of the brushes W^{66} , W^{67} from connection with their normal contacts 1714, 1715, the relay 1717 is held in its energized position.

Responsive to the energization of slow release relay 1601, by the closure of its contact 1, its upper winding is short-circuited, and a holding circuit therefor is established from ground, normal contact 4 of ST^8 , 70 brush W^{44} , its engaged contact 1403 of the office selector, lower winding and alternate contact 2 of slow release relay 1601, thence in multiple through the normal contacts 2 of the relays 1601 of all idle trunk lines of 75 the minor group, through winding of coil 1630, negative battery to ground, or, assuming the trunk line to be of some minor group other than the last minor group of the group, and all other trunk lines of the 80 minor group to be busy, from its alternate contact 2, through winding of relay GBC^9 of the minor group, winding of coil 1630, negative battery to ground, whereby the slow release relay 1601 is held in its energized position as long as the normal contact 4 of ST^8 remains closed.

The energization of relay 813, as last described, by the closure of its contact, establishes circuit for the magnet RM^8 of the 90 thousands section of the impulse transmitter, whereupon the brush thereof is caused to be restored, during which, responsive, to closures and openings of the contact 915 of the section, nine impulses of current are 95 transmitted through the winding of coil 817, whereby relay 1717, for each such closure of the contact 915, is deprived of current and deenergized, resulting, for each deenergization of the relay 1717, in the transmission of an impulse of current through the winding of the motor magnet MM^{13} of the thousands section of the decimal register from ground, upper normal contact of 1717, brush W^{68} , second contact 1716 from normal, 105 right-hand contact of RM^{13} , winding of MM^{13} , negative battery to ground, which causes the brush W^{68} to be rotated step by step to connection with its ninth passive contact 1801 from normal, connected with the 110 sixth line number indicator lamp of the thousands group.

Responsive to the first deenergization of relay 1717, as a result of the closure of contact 915 of the thousands section impulse 115 transmitter, circuit is established for the slow release relay 1719, from ground, lower normal contact of 1717, alternate contact 3 of 1718, winding of 1719, negative battery, to ground, which energizes and, by the opening of its normal contact, prevents the closing of circuit for the magnet MM^{12} , responsive to the transmission of the impulses through the contact 915.

During the return to normal of the 125 brushes of the thousands section of the impulse transmitter, after transmission of the impulses through its contact 915, circuit for the relay 1717 is continued and the relay energized a length of time sufficient to allow, 130

by the opening of its lower normal contact, the deenergization and return to normal of the slow release relay 1719, whereby circuit is established for the magnet MM¹², from 5 ground, upper alternate contact of 1717, normal contact of 1719, winding of MM¹², negative battery, to ground, which responds and rotates the brushes W⁶⁶ to W⁶⁸ inclusive out of connection with their second 10 and into engagement with their third set of contacts 1714 to 1716, inclusive.

Upon the return to normal of the brush of the thousands section of the impulse transmitter, circuit is established through 15 the contact of 813, for the magnet RM³ of the hundreds section of the impulse transmitter, whereby the brush of the section returns to normal and, in the manner described, transmits through its contact 915 20 three impulses of current through the winding of coil 817, whereby relay 1717, for each such closure of the contact 915 of the hundreds section, is deprived of current, resulting in three deenergizations and energizations 25 thereof, which transmits three impulses of current from ground, upper normal contact of 1717, brush W⁶⁸, its engaged third contact 1716, right-hand normal contact of RM¹², winding of MM¹³ of the hundreds section of the decimal register, negative battery, to ground, resulting in the movement of the brushes W⁷⁰ and W⁷¹ into 30 engagement with their third set of contacts 1802 and 1803, respectively, from normal. 35 Thereafter, during the return to normal of the brush of the hundreds section of the impulse transmitter, circuit through the winding of relay 1719 is interrupted, the relay deenergized and circuit established for 40 the magnet MM¹², which rotates the brushes W⁶⁶ to W⁶⁸ inclusive from connection with their third set of contacts to connection with their fourth set of contacts 1714 to 1716 inclusive.

45 When the brush of the hundreds section of the impulse transmitter reaches normal, the energizing circuit for magnet RM³ of the tens section of the impulse transmitter is established through contact of 813, and the 50 brush of the section started on its return to normal, transmitting, in the manner described, four impulses of current through its contact 915, resulting in four deenergizations and energizations of the relay 1717, 55 whereby four impulses of current are transmitted through the winding of magnet MM¹³ of the tens section of the decimal register, from ground, upper normal contact of 1717, brush W⁶⁸, its fourth contact 60 1716, contact of RM¹², winding of MM¹³, negative battery, to ground, which responds and rotates the brush W⁷² to connection with its fourth contact 1804 from normal, which is connected with the fourth indicator lamp

of the tens group of the line number lamp 65 indicators.

Thereafter, during the continued rotation of the brush of the tens section of the impulse transmitter to normal, the relay 1719 is deenergized, circuit established for the 70 magnet MM¹², and the brushes W⁶⁶ to W⁶⁸, inclusive, moved from connection with their fourth set of passive contacts to connection with their fifth set.

When the brush of the tens section of the impulse transmitter reaches normal, by the closure of contact 917 of the section, circuit is established for the magnet RM³ of the unit section, whereupon its brush returns to normal, during which six impulses 80 of current are transmitted through its contact 915, causing six deenergizations and energizations of the relay 1717, resulting in the transmission of six impulses of current through the winding of the magnet MM¹³ of the units section of the decimal register, from ground, upper normal contact of 1717, brush W⁶⁸, its fifth contact 1716, right-hand alternate contact of RM¹², winding of MM¹³, negative battery, 90 to ground, and the movement thereby of the brush W⁷³ into engagement with its sixth passive contact 1805 from normal, connected with the sixth indicator lamp of the units group. The rotation of the brush of the 95 units section of the impulse transmitter continuing, following the closures and interruptions of its contact 915, circuit for the flow of current through the winding of relay 1717 is maintained a length of time sufficient to cause the deenergization of relay 1719, and establish, by the closure of its normal contact, circuit for the motor-magnet MM¹², whereby the brushes W⁶⁶ to W⁶⁸ inclusive are rotated out of connection with their fifth set of contacts to connection with their sixth and last set of contacts 1714 to 1716 inclusive.

When the brush of the units section of the impulse transmitter reaches normal position, 110 the connecting circuit finder is, in the manner described, caused to be disconnected from the connecting circuit and restored to normal, and the relay 757 of the connecting circuit energized whereupon, by the closure 115 of its alternate contacts 2 and 3, the selected trunk line circuits, leading to the manual office are connected with the relay 746 and the right-hand windings of the repeating coil 753.

The energization of relay 757, by the interruption of its normal contact 1, interrupts connection between lamp 703 and interrupter I³, preventing thereby the further flashing of the lamp, and by the closure of 125 its alternate contact 1, the lamp 703 is, in the manner described, caused to burn steadily.

Upon movement of the brushes of the

decimal distributor into connection with their sixth set of passive contacts, a short circuit is placed around the winding of relay 1626, which may be traced from ground, 5 contact 4 of 1718, contact 1721, contact 3 of ST¹⁰, brush W⁶², its engaged passive contact 1711, normal contact 4 of 1624, normal contact 4 of 1617, to one terminal of the winding of 1626, the other terminal of which is 10 connected with ground, whereupon the relay 1626 is deenergized, and by the closure of its contact 2, circuit is established for the relay 1617 from ground, alternate contact 5 of 1616, normal contact 1 of 1622, contact 2 of 1626, contact 4 of 1625, winding of 1617, negative battery, to ground, which is actuated, and by the opening of its normal and closure of its alternate contact 1, the holding circuit for the relay 1625 is interrupted, 15 20 which deenergizes, connecting, by the closure of its normal contacts 1 and 2, the left-hand windings of the repeating coil 1609 and the windings of the relay 1618 with the interoffice trunk.

25 Responsive to the energization of the relay 1617, a holding circuit therefore is established from ground, alternate contact 3 of 1616, normal contact 1 of 1622, alternate contact and winding of 1617, negative battery, to ground, which maintains the relay energized, and by the opening of normal contacts 2 and 3 of the relay 1617 and the opening of alternate contacts 1 and 2 of relay 1625, the relay 1717 is disconnected from 30 the interoffice trunk. Also, as a result of the opening of the normal and closure of alternate contact 4 of the relay 1617, the previously traced path for the flow of current through the windings of relays 1626 35 and RC¹⁰ is interrupted and a holding circuit for the relay RC¹⁰ established from normal contact 2 of 1622, contact 1 of 1616, alternate contact 4 of 1617, contact 4 of 1624, passive contact 1711, brush W⁶² in engagement therewith, contact 3 of ST¹⁰, winding of relay RC¹⁰, negative battery, to ground, which holds the relay RC¹⁰ in its energized position after the interruption of contact 1721 of the decimal distributor.

40 45 As the deenergization of relay 1625, and, thereby, the connection of relay 1618 with the interoffice trunk, occurs before the brush of the units section of the impulse transmitter reaches normal, the holding circuit for the relay 1618 may be traced through the winding of relay 813 and coil 817; thereafter, upon the energization of relay 757, a holding circuit for the relay 1618 may be traced through the winding of relay 746, right-hand winding of coil 753 in series connection with negative battery. However, the relay 746 will not, owing to the high resistance of the left-hand winding of 1618, be energized sufficiently to interrupt its normal and close its alternate contact.

As the relay 1616 is slow to release, it will not be sufficiently deenergized during the interval between the deenergization of relay 1626 and the closure of circuit through its upper winding through the contact of relay 1618. 70

The deenergization of relay 1717, responsive to its disconnection from the interoffice trunk, through the contacts of relays 1617 and 1626, as described, interrupts the circuit through its lower alternate contact for the slow release relay 1718, which deenergizes and, by the opening of its alternate contact 3, interrupts circuit through the winding of slow release relay 1719, which 75 deenergizes and interrupts, upon the opening of its alternate contact, the then existing holding circuit through the winding of relay RC¹⁰, through the lower normal contact of 1717 and normal contact 3 of 1718. 85

The closure of the upper normal contact of 1717, following its deenergization as a result of the opening of the alternate contacts 1 and 2 of 1625, establishes a vibratory circuit for the magnet MM⁶ from ground, upper normal contact of 1717, brush W⁶³, its engaged sixth contact 1716, normal contact of relay T⁵, interrupter contact and winding of MM⁶, which responds and rotates the brushes W⁶⁵ to W⁶⁰ inclusive 90 step by step into and out of connection with their associated passive contacts 1703 to 1708 inclusive, until the brush W⁵⁰ engages the contact 1704 connected with the sixth contact 1714 then in engagement with brush W⁶⁶, when circuit is established for the relay T⁵ from ground, winding of relay T⁵, brush W⁵⁶, the engaged contact 1704, the sixth contact 1714, brush W⁶⁶ of the decimal distributor, winding of coil 1722, negative 95 battery to ground, which energizes and interrupts the vibratory circuit for the motor-magnet MM⁶, preventing further rotation of the brushes W⁶⁵ to W⁶⁰.

The closure of right-hand alternate contact of relay T⁵ connects ground with each of the brushes W⁵¹ to W⁶⁰ inclusive, and therefrom through the engaged contacts 1705 to 1708, inclusive, with brushes W⁶⁰, W⁵⁹, W⁵⁸ and W⁵⁷ of the sections of the 100 decimal register, and thence through their engaged passive contacts 1801 to 1805, inclusive, through the corresponding number indicator lamps to negative battery, whereupon the fifth lamp of the thousands 105 group, the third lamp of the hundreds group, the fourth lamp of the tens group and the sixth lamp of the units group are illuminated, visually indicating to the operator the numerical designation of the 110 substation with which connection is to be established.

The closure of left-hand alternate contact of T⁵ establishes circuit for the flow of current from ground, brush W⁵⁸, its engaged 115

sixth contact, left-hand alternate contact of T⁵, brush W⁵⁶, its engaged contact 1703, contact 3 of RC¹⁰, normal contact 2 of 1718 (now closed), brush W⁶⁵, its engaged contact 5 1713, alternate contact 2 of 1617, contact 3 of 1621, through lamp 1627, negative battery, to ground, which causes the illumination of the lamp and visually indicates to the operator the trunk line to be used in 10 establishing connection with the line of the substation indicated by the lighted lamps of the number indicator, whereupon, the operator, observing the lighted condition of the assignment lamp 1627 and the lighted ones 15 of the lamps of the number indicator, places the terminal 1602 of the plug switch into connection with the terminal 1607 of the multiple jack, before her, of the line of the called substation, and, as in manual practice, 20 ascertains the busy or idle condition of the line of the called substation. If busy, the operator will insert the plug switch into connection with the "busy back" jack 1631, to which is connected an interrupter I¹² 25 adapted to vibrate relay 1610, whereby, for each closure of its contact, the left-hand high resistance winding of relay 1618 will be short-circuited, and sufficient current will flow over the interoffice trunk through the 30 winding of relay 746 to cause its energization to an extent sufficient to interrupt its normal contact and close its alternate contact.

The initial closing of the alternate contact 35 of relay 746, responsive to the initial short-circuiting of the left-hand winding of the relay 1618, will establish the energizing circuit for the relay 758, whereby circuit for the flow of current through the lamp 703 40 will be interrupted and the lamp 704 connected with the normal contact of relay 746. Thereafter, so long as the plug switch remains in the "busy back" jack for each closure and opening of the contact of relay 45 1610, the lamp 704 will "flash" and visually indicate to the operator at the automatic call distributing office that the line of the called substation is busy and that connection cannot be established.

50 If, as is assumed, the line of the called substation, when tested, be found idle, the operator inserts the plug switch into the multiple jack, before her, of the line of the called substation, whereby terminals 1602, 55 1603 and 1604 of the plug switch are connected with the terminals 1605, 1606 and 1607 respectively of the multiple jack of the line of the called substation. The connection of 1604 with 1607 establishes circuit for 60 the flow of current from ground, winding of CO⁴, 1607, 1604, winding of 1622, negative battery, to ground, which energizes the relays CO⁴ and 1622, whereupon, by the opening of the contacts of CO⁴, the relay LR⁴ is dis-

connected from the line of the called substation. 65

The opening of normal contact 1 of 1622 interrupts the holding circuit for the relay 1617, which deenergizes and interrupts, by the opening of its alternate contact 2, the 70 circuit for the flow of current through the lamp 1627, which is extinguished. The closure of alternate contact 3 of 1622 establishes circuit for the flow of current through the left-hand winding of differentially 75 wound relay 1615 from ground, alternate contact 3 of 1622, normal contact of 1621, left-hand winding of 1615, negative battery, to ground, and as circuit for the flow of current, through closed contact of 1618, through 80 the right-hand winding of 1615, is now established, the relay is deenergized, its alternate contact opened and its normal contacts closed.

The closure of contact 3 of 1615 establishes an initial energizing circuit for the relay 1619 from ground, interrupter I⁶, contact 3 of 1615, contact 4 of 1620 (the relay 1620 now energized over circuit for the flow of current from ground, alternate contact 3 90 of 1622, contact of GTR², contact 3 and lower winding of 1620, negative battery, to ground), normal contact 3 and winding of 1619, negative battery, to ground, whereupon a holding circuit therefor is established from ground, alternate contact 3 of 1622, normal contact 1 of 1621, alternate contact 3 and winding of 1619, negative battery, to ground. 95

The closure of alternate contact 1 of 1622 100 establishes a circuit for the flow of current through the winding of relay 1623 from ground, alternate contact 3 of 1616, alternate contact 1 of 1622, normal contact 1 and winding of 1623, negative battery to ground, 105 whereby the relay is actuated and a holding circuit established therefor, from ground, alternate contact 3 of 1616 alternate contact 1 and winding of 1623, negative battery, to ground, which maintains the relay in its 110 energized position as long as the relay 1616 remains in its energized position.

Restoration of number indicating device.

The opening of normal contact 2 of 1622 115 interrupts the then existing holding circuit for the relay RC¹⁰, which is deenergized establishing a vibratory circuit for the motor-magnet MM¹² from ground, normal contact 2 of RC¹⁰ contact 1720 (now closed), interrupter contact and winding of MM¹², 120 negative battery, to ground, which responds and rotates the brushes W⁶⁶ to W⁵⁶, inclusive, out of connection with their associated sixth set of contacts to normal, when, by the 125 opening of contact 1720, the circuit through magnet MM¹² is interrupted and its further actuation prevented.

The closure of normal contact 1 of RC^{10} establishes circuit for the relay ST^{10} from ground, normal contact of IT^{10} , normal contact of PON^{10} , normal contact 1 of RC^{10} , alternate contact 2 of RR^{10} , winding of ST^{10} , negative battery, to ground, which responds and, by the closure of its contact 2, establishes the previously described vibratory circuit through magnet SM^{10} , whereupon the brushes W^{62} to W^{65} , inclusive, of the cord finder, are rotated step by step until they reach the position one step beyond the last set of contacts 1710 to 1713 inclusive of the row, when the brush W^{61} is rotated to normal and brushes W^{62} to W^{65} inclusive, to the position above normal, whereupon, by the opening of the alternate contact of PON^{10} , the traced circuits through the windings of relays RR^{10} and ST^{10} are interrupted and the relays deenergized, whereby, as a result of the opening of contact 2 of ST^{10} , the vibratory circuit through the winding of magnet SM^{10} is interrupted and its further actuation prevented.

Simultaneously with the opening of alternate contact of PON^{10} , the brushes W^{62} to W^{65} inclusive are rotated to normal position, whereupon the contact of SON^{10} is closed and the switch placed in condition, when allotted, to be utilized to again select an associated interoffice trunk.

The closure of normal contact 4 of RR^{10} establishes circuits for the flow of current through the windings of the restoring magnets RM^{13} of each section of the decimal register from ground, normal contact 4 of RR^{10} , thence through the left-hand contacts of ON and winding of magnet RM^{13} of each section, negative battery, to ground, which are actuated and the brushes, in the manner described, restored to normal, whereupon, by the opening of the left-hand contact of ON of each section, the circuit through its associated magnet RM^{13} is interrupted and the magnet deenergized, placing, thereby, the register in its normal position.

Responsive to the disconnection of brush W^{66} of the decimal distributor from connection with its sixth contact, the circuit through relay T^6 of the allotter of assignment lamps and called line number indicators is interrupted, the relay deenergized, and by the closure of its normal contact the magnet MM^6 is placed in condition to be, upon closure of its circuit, actuated to move the brushes of the allotter to connection with the next succeeding set of passive contacts.

Establishment of connections from automatic call distributing offices to manual offices—continued.

The deenergization of relay 1615, responsive to the energization of relay 1622, by the opening of its contact 2, interrupts the ini-

tial energizing circuit through the relay 1620 (then existing), and by the closure of contact 3 of 1615, interrupter I^6 is connected with the winding of relay 1619, which may be traced from ground, interrupter I^6 , contact 3 of 1615, contact 4 of 1620, normal contact 3 and winding of 1619, negative battery, to ground, with the result that when the brushes of the interrupter I^6 engage any of their live segments, the relay 1619 is energized and a holding circuit established therefor from ground, alternate contact 3 of 1622, normal contact 1 of 1621, alternate contact 3 and winding of 1619, negative battery, to ground, which holds the relay in its energized position as long as the relay 1621 remains deenergized and the relay 1622 energized.

The closure of alternate contacts 1 and 2 of the relay 1619 connects signaling current with the line of the called substation over a circuit from ground, alternate contact 1 of 1619, alternate contact 1 of 1620, plug switch terminal 1602 in connection with jack terminal 1605, thence over the line, through the signal bells thereof, returning through jack terminal 1606, plug switch terminal 1603 in connection therewith, alternate contact 2 of 1620, contact 2 of 1619, contact 1 of 1615, winding of relay GTR^2 to the grounded source of signaling current (not shown), whereby the signal bells of the substation are actuated.

Before proceeding further, it may be stated that the relation of the segments of the interrupter I^6 to the interrupter of the signaling device (not shown) is such that signaling current will not be connected to the line of the called substation until at least two seconds after energization of the relay 1619, in response to the closure of its circuit through the interrupter I^6 . It also may be reiterated that the characteristics of the relay GTR^2 are such that it will not be sufficiently energized when its winding is in series connection with the windings of the signal device of a substation. When the called party responds by removing the receiver from the switchhook, the flow of signaling current through the winding of GTR^2 is increased sufficiently to cause the actuation of the relay and thereby the opening of its contact, whereupon the holding circuit through relay 1620 is interrupted, the relay deenergized, and by the opening of its alternate contacts and the closure of its normal contacts 1 and 2, signaling current is disconnected from the line of the called substation and the right-hand windings of repeating coil 1609, negative battery and the winding of relay 1610 are serially connected therewith, whereupon the relay 1610 is energized over a circuit from ground, upper right-hand winding of 1609, normal contact 1 of 1620, contact of 1602 in engagement

with contact 1605, over the line and through the transmitter, switchhook contact and right-hand winding of the induction coil of the substation, returning over the other strand of the line through contact 1602 in engagement with contact 1603, normal contact 2 of 1620, winding of 1610, lower right-hand winding of 1609, negative battery, to ground, which, by the closure of its contact, 10 short-circuits the left-hand high resistance winding of relay 1618, resulting in the increase of flow of current over the interoffice trunk, through the relay 746 of the connecting circuit at the automatic call distributing office, to an extent sufficient to cause its actuation and thereby the opening of its normal and closure of its alternate contact, whereby the energizing circuit through the left-hand winding of 758 is established, the 15 relay actuated and, by the opening of its normal contact 3, the then existing flow of current through lamp 703 interrupted, whereby the lamp is extinguished.

25 *Restoration of connection between automatic call distributing office and manual office.*

After the completion of conversation, when the receiver at the called substation is replaced on the switchhook, the flow of current through relay 1610 is interrupted, the relay deenergized, its contact opened and the short-circuit removed from around the left-hand high resistance winding of relay 1618; whereby the flow of current through relay 30 746 is decreased to an extent sufficient to cause its actuation, whereupon, by the opening of its alternate and closure of its normal contact, circuit for the flow of current through lamp 704 is established, whereby 35 the lamp is illuminated, visually indicating to the operator that the called subscriber has "hung up." The operator, observing the lighted condition of the lamp 704, if the calling party has also "hung up" (which will 40 be indicated by the lighted condition of the lamp 702), actuates from normal the proper one of the disconnect keys, whereupon all apparatus at the automatic call distributing office employed in establishing the connection 45 50 not previously restored, is disconnected and restored in the manner described in reference to interoffice connections.

Responsive to the releasing operation of the apparatus at the automatic call distributing office, the traced circuit through the winding of relay 1618 is interrupted, the relay deenergized and its contact opened, whereby the holding circuit through the upper winding of relay 1616 is interrupted, and 55 60 circuit for the flow of current through the right-hand winding of 1615 interrupted, resulting in the deenergization of relay 1616 and in the energization of relay 1615.

The closure of normal contact 3 of relay 65 1616 establishes circuit for the flow of cur-

rent through winding of relay 1621, from ground, normal contact 3 of 1616, contact 4 of 1622, alternate contact and winding of 1621, negative battery, to ground, which responds and establishes a holding circuit 70 therefor from ground, alternate contact 3 of 1622, alternate contact 2 and winding of 1621, negative battery, to ground, whereby the relay is held in its energized position as long as the plug switch remains in connection with the jack of the line of the called substation. 75

The closure of alternate contact 4 of 1621 establishes circuit for the flow of current through lamp 1628, which is illuminated 80 and indicates to the operator that disconnection should take place. The opening of normal contact 1 of 1621 interrupts the previously traced circuit for the flow of current through the left-hand winding of relay 1615 and the winding of relay 1619, 85 which are deenergized.

The operator, observing the lighted condition of lamp 1628, removes the plug switch from connection with the multiple 90 jack of the line of the called substation, whereupon circuit through relays CO⁴ and 1622 is interrupted, the relays deenergized, which in respect to relay CO⁴, by the closure of its contacts, connects the relay LR⁴ is 95 connected with the line whereupon it may be actuated, responsive to the removal of the receiver from the switchhook at the substation thereof.

The deenergization of relay 1622, by the 100 opening of its contact 4, interrupts circuit for the relay 1621, which is deenergized, and by the opening of its contact 4 interrupts circuit for the flow of current through lamp 1628, which is extinguished. 105

Re-ringing the called party in a connection between an automatic call distributing office and a manual office.

Assuming, during the existence of a connection of a calling substation terminating in an automatic call distributing office with a called substation terminating in a manual office, it be desired to recall the called party, the operator at the automatic call distributing office, by actuating the key 709 of the connecting circuit, causes, in the manner described, the interruption of connection of ground and upper right-hand winding of repeating coil 753 with the interoffice trunk 120 and the relay 1618, and establishes a vibratory circuit for the relay 735, whereby, in response to the repeated opening and closing of its contact, the relay 1618 is caused to vibrate in synchronism therewith, resulting in the opening and closing of its contact, and thereby interrupting and closing the circuit for the flow of current through the right-hand winding of relay 1615, responsive to which the relay 1615 is ener- 125 130

gized and deenergized, with the result that upon its first energization, circuit is established over the previously traced path through the upper winding of relay 1620, 5 which responds, establishes its holding circuit, disconnects, by the opening of its normal and closure of its alternate contacts 1 and 2, negative battery, right-hand windings of repeating coil 1609 and relay 1610 from 10 the line of the called substation and, in the manner described, connects signaling current with the line.

After the restoration of the key 709 and the response at the called substation, by the 15 removal of the receiver from the switch-hook, the relays 1610, 746 and 758 are again energized, and the talking connection established as originally set forth.

Should the operator at the manual office 20 inadvertently disconnect a plug switch from the jack of a called line prior to disconnection by the operator at the automatic call distributing office (that is, before the illumination of the lamp 1628), circuits through 25 the relays 1622 and CO⁴ will be interrupted and the relays deenergized, which, by the opening of alternate contact 3 of the relay 1622, will interrupt the flow of current through the left-hand winding of differentially wound relay 1615, whereby, owing to 30 the flow of current at this time through its right-hand winding, via contact of 1618 and alternate contact 2 of 1616, the relay 1615 will be energized and establish circuit 35 for the flow of current through the winding of relay 1624 from ground, normal contact 3 of 1622, contact 2 of 1623, normal contact 3 and winding of 1624, negative battery, to ground, which will energize and 40 establish a holding circuit therefor from ground, alternate contact 3 of 1616, alternate contact 1 and winding of 1623, negative battery, to ground, whereby the relay will be held in its energized position as long 45 as the alternate contact 3 of 1616 remains closed.

Premature disconnection of established connection between an automatic call distributing office and a manual office at the manual office.

Responsive to the energization of relay 1624, circuit will be established for the flow of current through the lamp 1628, from 55 ground, interrupter I¹, contact 3 of 1623, contact 2 of 1624, normal contact 4 of 1621, through lamp 1628, negative battery, to ground, whereby the lamp 1628 will be, responsive to each closure and interruption 60 of the brushes I¹ with their live segments, caused to flash to indicate to the operator that the connection was prematurely interrupted; whereupon the operator may connect the plug switch with a spring jack 65 connected with any desirable device, which

will enable an attendant to ascertain from the subscriber at the calling substation the number of the called substation. Thereafter, the operator may reestablish connection of the plug switch with the multiple 70 jack of the line of the called substation. Or, in the event of failure of reconnection of the plug with the jack of the line of the called substation, upon disconnection by the operator at the automatic call distributing 75 office, the relay 1618 will, in the manner described, be deenergized, its contact opened, and the holding circuit through the upper winding of relay 1616 thereby interrupted, which will cause the deenergization of the 80 relays 1615, 1620, 1623 and 1624 and thus restore the trunk line to the condition whereby it may be selected and connected with the line of the desired called substation responsive to some other call. 85

Abandonment of uncompleted connection at call distributing office.

Should the operator at the automatic call distributing office, after actuation of the 90 recording keys and before the completion of the operation of the decimal register to cause the illumination of the line number indicator lamps, cause disconnection from the selected trunk, the circuit for the flow of 95 current through the winding of relay 1717 will be interrupted, the relay deenergized, circuit for slow release relay 1718 interrupted and circuit for the slow release relay 1719 established, which will, in the manner 100 described, short-circuit the winding of relay 1626, which will be deenergized and, by the closure of its contact 2, establish an energizing circuit for the relay 1617, which, responding by the closure of its alternate contact 3, will establish circuit for the relay 1624 105 from ground, alternate contact 2 of RC¹⁰, brush W⁶⁷, its engaged contact 1715, alternate contact of relay 1718, contact 4 of RC¹⁰, contact 3 of RR¹⁰, brush W⁶⁴, its passive contact 1712, alternate contact 3 of 1617, normal contact 3 of 1624, negative battery to ground, which responding, following the deenergization of 1719 and the opening of the lower contact thereof, the holding circuit there-through for the relay RC¹⁰ 110 will be interrupted, following which, in the manner described, the cord finder will be disconnected from the trunk and restored to normal.

The closure of normal contact 2 of RC¹⁰ 120 will establish the previously described vibratory circuit through contact 1720 for magnet MM¹², which responding, will rotate the brushes W⁶⁶ to W⁶⁸ inclusive step by step into and out of connection with their associated contacts to normal position, whereupon, by the opening of contact 1720, the circuit of the magnet will be interrupted and its further actuation prevented. 125

Following the deenergization of slow re- 130

lease relay 1616, the described holding circuits through relays 1617 and 1624 will be interrupted, the relays thereby deenergized, and the trunk line placed in condition to be used in establishing some other connection.

Seizure of inter-office trunk before finally being freed from a previous connection at the manual office.

10 After the disconnection of the apparatus at the automatic call distributing office from the interoffice trunk and before disconnection by the operator of the plug switch of such trunk from connection with the line 15 of a called substation, should the trunk be again selected by an office selector, which is possible, the relay 1617 will be energized and, in the manner described, the trunk selected by a cord finder, whereupon relay 20 1626 will be energized followed by the energization of relay 1616, in which condition the apparatus will be held until disconnection of the plug switch from the jack of the substation line; whereupon, responsive to the 25 deenergization of the relay 1622 followed by the deenergization of the relay 1621, and thereby interruption of the flow of current through lamp 1628, the previously traced energizing circuit for the relay 1625 will be 30 established and the relay 1717 connected with the trunk. Thereafter, responsive to the transmission of impulses from the impulse transmitter at the automatic call distributing office, the number of the then desired 35 called substation will be registered on the decimal register, the line number indicator lamps and the lamp 1627 illuminated, whereupon the connection of the plug with the multiple jack, before the operator, of the 40 line of the then desired call substation may be established in the manner described.

Establishment of connection over manual incoming trunk lines.

45 Considering now the operation of establishing connection of the line of a calling substation terminating in a manual office with the line of a called substation terminating in a call distributing office, and having 50 particular reference to circuits and apparatus illustrated in Figs. 12—13—19 (Parts 1 and 2) 20 and 21 (Parts 1 and 2).

An operator in a manual office receiving a 55 request from a calling substation of a line terminating therein for connection with a called substation, the line of which terminates in an automatic call distributing office, verbally, by "order wire" (not shown), transmits the numerical designation of the 60 desired called substation, which is assumed to be 5346, to an operator at the automatic call distributing office, in which the line of the called substation terminates, and before whom appears, in the form of keys and signaling lamps, a plurality of trunk lines ex-

tending between the manual office, in which terminates the line of the calling substation, and the automatic call distributing office, in which terminates the line of the called substation, which are herein termed "manual incoming trunk lines," adapted to complete connections of calling substations terminating in the manual office with substations, as called substations, terminating in the automatic call distributing office.

The operator at the automatic call distributing office, upon ascertaining the number of the called substation, verbally assigns an idle one of the trunk lines by means of the order wire circuit, informing, the operator at the manual office the number of such assigned trunk line, whereupon the operator at the manual office connects the calling plug switch terminal (not shown) of the pair to be used in establishing the connection with a multiple jack (not shown) appearing before her, corresponding to and connected with the assigned trunk line, which establishes circuit for the relay 1907, from ground, over the upper limb of the trunk line, through the upper left-hand winding of repeating coil 1906, windings of relay 1907, lower left-hand winding of 1906, thence over the lower limb of the trunk line, through the supervisory apparatus of the calling cord of the pair, battery to ground, which is actuated and, by the closure of its contact, establishes circuit for the flow of current through the lower winding of relay 1910, which energizes and establishes circuit for the flow of current through the lamp 1904 from ground, normal contact 3 of relay 1914, normal contact 1 of relay 1913, alternate contact 1 of 1910, normal contact 1 of relay 1911, lamp 1904, negative battery to ground, illuminating thereby the lamp 1904, thus indicating to the operator at the automatic call distributing office the connection of a connecting plug switch at the manual office with the multiple jack of the trunk line.

The operator at the automatic call distributing office, after ascertaining the number of the line of the desired substation and assigning the trunk line, actuates the assignment key 1901 of the assigned trunk, whereupon circuit is established for the relay 1912, from ground, normal contact 3 of 1914, normal contact 1 of 1913, right-hand contact of 1901, winding of 1912, negative battery to ground, and an energizing circuit for the common relay 2001 from ground, left-hand contact of 1901, negative battery to ground, whereupon, in reference to 1912, a holding circuit therefor is established from ground, normal contact 3 of 1914, normal contact 1 of 1913, left-hand contact and winding of 1912, negative battery to ground, which holds the relay in its energized position after restoration of the assignment key, and by

the opening of its normal contact disconnects ground from the multiply connected passive contacts 2005 of the associated manual incoming trunk finders, rendering the 5 trunk selectable by such finder switches. Also by the closure of the right-hand alternate contact of 1912, circuit is established for the relay GBC¹² of the corresponding finder group which energizes, disconnecting 10 ground from the multiply connected group test passive contacts 2004, rendering the corresponding finder group selectable by the associated manual incoming trunk finders, and establishes the initial energizing circuit for 15 the relay PT¹³ of the then allotted manual incoming trunk finder from ground, alternate contact of GBC¹², thence over the common conductor, brush W⁸⁰, its engaged passive contact 2101 of the allotter of the manual incoming trunk finders, normal contact 20 of PON¹³, winding of PT¹³, negative battery to ground, which is energized, establishing, through its right-hand alternate contact, a vibratory circuit for the magnet 25 PM¹³, which rotates the brush W⁸⁴ to connection with its first passive contact 2004, the multiply connected test terminal corresponding to the first manual incoming 30 trunk finder group of the associated group of trunk lines, and the brushes W⁸⁵ to W⁸⁸, inclusive, opposite to passive contacts 2005 to 2008 inclusive, multiply connected with the manual incoming trunks of such first 35 manual incoming trunk finder group, during which movement of the brushes, if the assigned trunk line be included in the first finder group, circuit through the relay PT¹³ will (owing to the energized condition of the relay GBC¹² of the group and the interruption 40 of its normal contact, whereby ground is disconnected from the contact 2004) be interrupted, the relay returned to normal, whereupon brushes W⁸⁵ to W⁸⁸ inclusive will be moved into and out of connection with their associated sets of passive 45 contacts 2005 to 2008 until the set multiply connected with the assigned trunk is engaged, when the brushes will be brought to rest in connection therewith. Assuming, 50 however, the trunk line assigned to be included in some manual incoming trunk finder group other than the first, then prior to the opening of normal contact of PON¹³, by the engagement of brush W⁸⁴ with the first contact 2004, a holding circuit for the 55 relay PT¹³ is established from ground, normal contact of GBC¹² of the first manual incoming trunk finder group, multiply connected passive contact 2004, brush W⁸⁴, left-hand alternate contact and winding of PT¹³, negative battery to ground, which maintains the relay PT¹³ in its energized position and the vibratory circuit through PM¹³ closed, whereby the brushes are rotated step by step 60 in their primary selecting operation until 65

the brush W⁸⁴ engages contact 2004 corresponding to the finder group in which is included the trunk of the actuated assignment key 1901, whereupon, owing to the interruption of the normal contact of the corresponding relay GBC¹², holding circuit for the relay PT¹³ is interrupted, the relay de-energized and the vibratory circuit through its right-hand alternate contact for the magnet PM¹³ interrupted, preventing further 70 actuation of the magnet PM¹³.

Following the de-energization of PT¹³, circuit is established for the relay ST¹³ from ground, normal contact of PT¹³, alternate contact of PON¹³, normal contact of SON¹³, 80 winding of ST¹³, negative battery to ground, which energizes, establishing a vibratory circuit for the magnet SM¹³ from ground, alternate contact 3 of ST¹³, interrupter contact and winding of SM¹³, which responds 85 and rotates the brushes W⁸⁵ to W⁸⁸, inclusive, into connection with their associated first set of contacts 2005 to 2008, respectively, of the selected row, multiple terminals of the first trunk line of the corresponding 90 finder group; whereupon, by the closure of alternate contact of SON¹³, the initial energizing circuit for the relay RC¹³ is established from ground, normal contact of PT¹³, alternate contact of PON¹³, alternate contact 95 of SON¹³, normal contact 2 of RR¹³, contact 1 of 2010, winding of RC¹³, negative battery to ground. Also during such movement of the brushes, by the opening of normal contact of SON¹³, if the first set of contacts 2005 to 2008 inclusive be the multiple 100 terminals of the trunk line of the actuated assignment key 1901, circuit through relay ST¹³ will be interrupted, the relay de-energized and the vibratory circuit through 105 magnet SM¹³ interrupted.

Assuming, however, the trunk line of the actuated key 1901 to be other than the one connected with the first set of passive contacts 2005 to 2008, inclusive, then prior to 110 the opening of the normal contact of SON¹³, by the engagement of brush W⁸⁵ with the passive contact of 2005, a holding circuit for the relay ST¹³ is established from ground, normal contact of relay 1912 of the first 115 trunk line, multiply connected terminal 2005, brush W⁸⁵ in engagement therewith, alternate contact 1 of ST¹³, normal contact 1 of RR¹³, winding of ST¹³, negative battery to ground, which holds the relay in its 120 energized position, whereby the vibratory circuit for the magnet SM¹³ is maintained and the brushes W⁸⁵ to W⁸⁸, inclusive, rotated out of connection with their first set of passive contacts into connection with 125 their second set, and so on until the set corresponding to the trunk of the actuated key 1901 is engaged, when, owing to the interruption of the normal contact of its relay 1912, the holding circuit for the relay ST¹³ 130

- is interrupted, the relay deenergized, and by the opening of its alternate contact 3, the vibratory circuit through magnet SM^{13} interrupted, whereby its further actuation is 65 prevented, leaving the brushes W^{85} to W^{88} , inclusive, in connection with the passive contacts 2005 to 2008, inclusive, respectively, multiple terminals of the assigned trunk, whereupon circuit is established for relay 5 RR^{12} from ground, normal contact 3 of ST^{13} , contact 2 of RC^{13} , winding of RR^{12} , negative battery to ground, which energizes and establishes a holding circuit therefor from ground, normal contact of PT^{12} , alternate 10 contact of PON^{12} , alternate contact and winding of RR^{12} , negative battery to ground, which holds the relay in its energized position as long as the alternate contact of PON^{12} remains closed. 15
- 20 The closure of normal contact 1 of ST^{12} connects ground with the test brush W^{85} and the engaged contact 2005, preventing the selection of the selected manual incoming trunk circuit, pending the release of relay 25 1912 by any other manual incoming trunk finder.

The opening of the normal and closure of the alternate contact 2 of relay RR^{12} 30 interrupts the traced energizing circuit for the relay RC^{12} and establishes a holding circuit therefor from ground, contact of 2001, normal contact 1 of RR^{12} , left-hand contact of disconnect key 1903, multiply connected 35 passive contact 2006, brush W^{86} in engagement therewith, contact 2 of ST^{12} , alternate contact 2 of RR^{12} , contact 1 of 2010, winding of RC^{12} , negative battery to ground, which will maintain the relay RC^{12} in its energized position unless, prior to the energization of relay RR^{12} , as hereinafter described, the assignment key of another manual incoming trunk line of the group be actuated from normal.

The operator, after actuation of the assignment key of a trunk line, actuates the recording keys 2106 corresponding to the numerical designation of the substation with which connection is to be established—that is, the fifth, third, fourth and sixth key of the thousands, hundreds, tens and units group respectively, thereby establishing circuit for the flow of current through the corresponding magnets 2112, from ground, right-hand master contact 2114 of the 55 thousands group, right-hand master contact 2114 of the units group, thence in multiple through the sixth, fourth, third and fifth magnets 2112 of the units, tens, hundreds and thousands section respectively of the recorder, negative battery to ground. The magnets 2112 of each section responding, by the closure of master contacts 2113 of each section, circuit is established for the magnet CM^{12} of the allotted division of the recorder 60 from ground, contact 2113 of the units section, thence in series through the corresponding contacts of the tens, hundreds and thousands sections, brush W^{88} , its engaged passive contact 2104, winding of CM^{12} , negative battery to ground, which energizes and closes the fifth, third, fourth and sixth contact 2108 of the thousands, hundreds, tens and units sections respectively of the allotted division. Simultaneously therewith, by the closure of master contact 2129 of the division, circuit for the flow of current through the right-hand winding of the relay 70 2114 is established and maintained until energization of magnet RM^{12} , which, by the closure of its contact 4, establishes the energizing circuit for the restoring magnets RM^{12} of each group of recording keys from ground, contact 4 of 2114, passive contact of 75 2102, brush W^{81} in engagement therewith, normal contact of T^{12} , thence in multiple through the master contacts 2114 (now closed), winding of each magnet RM^{12} , negative battery to ground, which respond and release the actuated key of their corresponding group; whereupon, by opening of 80 contacts 2114, the traced energizing circuit through the magnets 2112 is interrupted, the magnets deenergized and their master contacts 2113 opened, interrupting thereby the circuit for the magnet CM^{12} .

The closure of contact 2 of 2114 establishes circuit from ground, contact 2 of 2114, thence in multiple through the contact 913, interrupter contact and winding of magnet MM^2 of each section of the impulse transmitter, negative battery to ground. The magnet MM^2 of each section energizes and rotates its brush W^{29} one step from normal, whereupon, by the opening of its contact 913, the initial energizing circuit is interrupted, and by the closure of its contact 912 an alternate vibratory circuit therefor is established from ground, contact 912, outer normal contact 2 of 924, interrupter contact and winding of MM^2 , negative battery to 95 ground, as a result of which the brush of each section of the impulse transmitter is rotated step by step until the passive contact 911 connected with the closed contact of the associated section of the recorder is engaged, 100 when the initial energizing circuit of its relay 924 is established from ground, closed contact 2108, brush W^{29} , inner normal contact 2 and winding of 924, negative battery to ground. The relay 924 responding, by 105 the opening of its outer normal contact 2, interrupts circuit through the motor-magnet MM^2 , preventing thereby its further actuation and establishes holding circuit from ground, its contact 912, alternate contact 2 110 and winding of 924, negative battery to ground, which holds the relay in its energized position as long as contact 912 remains 115

closed, or, in other words, as long as its associated brush W^{29} remains in off-normal position.

Responsive to the energization of all relays 924 of the impulse transmitter, by the opening of their normal and closure of their alternate contacts 1, short circuit is removed from around the left-hand winding of relay 2013 and a circuit therefor established from ground, right-hand winding of 2013, in multiple through the alternate contact 1 of each relay 924, winding of coil 2016, negative battery to ground, which energizes and, by the closure of its contact 2, circuit is established 10 over the traced path in multiple with winding of 2016, through the left-hand winding of 2013, negative battery to ground, which maintains the relay in its energized position as long as any of the relays 924 remain energized.

Again referring to the initial energization of 2014, circuit is established for the relay 2009 from ground, normal contact of PT^{13} , alternate contact of PON^{13} , alternate contact 3 of RC^{13} , contact 1 of 2014, contact 4 of RR^{12} , winding of 2009, negative battery to ground, which is energized and establishes circuit for the relay T^{14} from ground, contact 2 of 2009, passive contact 2103, brush W^{32} in engagement therewith, winding of T^{14} , negative battery to ground, which is actuated, whereby a vibratory circuit for the magnet MM^{14} is established from ground, right-hand alternate contact of T^{14} , interrupter contact and winding of MM^{14} , negative battery to ground, which responds and, in the manner described, rotates the brushes W^{30} to W^{33} inclusive out of connection with their then engaged passive contacts 2101 to 30 2104, inclusive, respectively, and, thereafter, step-by-step into and out of connection with their succeeding passive contacts until brush W^{32} engages a contact 2103 corresponding to a manual incoming trunk finder, then in 40 normal position and with which is associated an impulse transmitter and a division of the recorder also, at the time, in their normal positions: whereupon, owing to the absence of ground connection with the contact 2103, through contact 2 of 2009 or contact 4 of 2010, circuit through T^{14} is interrupted, its alternate contacts opened, interrupting the vibratory circuit for MM^{14} , preventing its further actuation and, thereby, the further 50 movement of the brushes W^{30} to W^{33} , inclusive.

During the energization of T^{14} and the rotation of the brushes of the allotter, as a result thereof, by the closure of left-hand alternate contact of T^{14} , ground is connected with the contacts 2114 of each group of recording keys 2106, with the result that, should a key of any group be actuated from normal, a circuit for its associated restoring magnet RM^{14} will, upon the closure of the

master contact 2114, be established, the magnet energized and the actuated key prevented from being locked in its actuated position.

Following the energization of 2009, circuit 70 is established for the flow of current from ground, winding of relay 2012, alternate contact 1 of RC^{13} , contact 4 of 2009, brush W^{38} , its engaged passive contact 2008, normal contact 1 of 1909, normal contact of PON^{13} , right-hand winding of relay RR^{12} , negative battery to ground, energizing the relays 2012 and RR^{12} , which, in respect to RR^{12} , establishes a holding circuit therefor from ground, normal contact 4 of 1909, 80 right-hand contact of disconnect key 1903, normal contact of holding key 1902, normal contact 3 of 1911, contact 2 and left-hand winding of RR^{12} , negative battery to ground. The closure of contact 3 of RR^{12} establishes 85 circuit for the flow of current through the left-hand winding of differentially wound relay 1915, which is energized and establishes circuit for the relay 1916 from ground, contact 3 of RR^{12} , alternate contact 2 of 90 1915, winding of 1916, negative battery to ground, which is actuated, establishing a holding circuit therefor from ground, contact 3 of RR^{12} , contact of GTR^3 , contact 2 and winding of 1916, negative battery to 95 ground, which holds the relay in its energized position as long as the contact of GTR^3 remains closed or until the deenergization of relay RR^{12} .

By the opening of the normal and closure 100 of the alternate contact 1 of RR^{12} , the previously traced holding circuit for the relay RC^{13} is interrupted and a substitute circuit established therefor, in series with winding of 1913, from ground, winding of 1913, alternate contact 1 of RR^{12} , left-hand contact of 105 1903, passive contact of 2006, brush W^{30} now in engagement therewith, alternate contact 2 of RR^{13} , contact 1 of 2009, winding of RC^{13} , negative battery to ground, which 110 holds the relay RC^{13} in its energized position and energizes relay 1913, whereupon, by the opening of normal contact 1 of 1913, the holding circuit then existing for the relay 1912 is interrupted, the relay deenergized, 115 following which, by the opening of its alternate contact, circuit for relay GBC^{12} of the finder group is interrupted, which deenergizes, interrupting the previously traced starting circuit for the manual incoming 120 trunk finders through brush W^{30} and contact of 2101, and connects ground with the corresponding group test contact 2004 to prevent the selection of the finder group by any manual incoming trunk finder as long as 125 the relay GBC^{12} remains deenergized; and assuming the operator at the manual office to have established connection with the trunk line, the then existing path for the flow of current through the lamp 1904 is inter- 130

rupted and the lamp extinguished. The closure of alternate contact 3 of 1913, establishes circuit from ground, interrupter I^{10} , alternate contact 3 of 1913, contact 2 of 5 1911, lamp 1905, negative battery to ground, resulting, for each closure and interruption of the brushes of the interrupter I^{10} with the live segments of the commutator thereof, in the flashing of the lamp 1905, visually indicating to the operator the connection of an 10 impulse transmitter with the trunk line.

Responsive to the energization of relay 2013, circuit is established for the flow of current through the left-hand winding of 15 2014 from ground, contact 4 of 2013, contact 3 and left-hand winding of 2014, negative battery to ground, which holds the relay in its energized position after the opening of the master contact 2129 of the division of 20 the recorder as long as the relay 2013 remains energized. Also by the closure of the contact 4 of 2013, circuit is established for the magnet RM^{16} from ground, contact 4 of 2013, winding of RM^{16} , negative battery 25 to ground, which is actuated and, in the manner described in connection with the description of Figs. 34, 35 and 36, interrupts the connection of the closed contacts 2108 of each section of the corresponding 30 division of the recorder.

The closure of contact 3 of 2013 establishes circuit for the flow of current through the left-hand winding of relay 2010, which is actuated, establishing a holding circuit 35 therefor from ground, normal contact of PT^{13} , alternate contact of PON^{13} , contact 3 and right-hand winding of 2010, negative battery to ground, which holds the relay in its energized position as long as the alternate 40 contact of PON^{13} remains closed.

The closure of contact 4 of 2010 connects ground with the passive contact 2103, whereby, after the deenergization of relay 2009 and the opening of its contact 2, the brushes 45 of the allotter are prevented from coming to rest in engagement with their corresponding associated set of passive contacts.

The closure of contact 1 of 2013 establishes the initial energizing circuit of the 50 magnet RM^3 of the thousands section of the impulse transmitter from ground, contact 1 of 2013, contact of 2012 (now energized in series with the right-hand winding of RR^{12} of the manual incoming trunk selector), contact 3 of 924, normal contact and winding of RM^3 , negative battery to ground, which responds and by the opening of its normal and the closure of its right-hand alternate contact, a holding circuit therefor, 55 through contact 912 of the section, is established, which holds the magnet in its energized position until the return to normal of the brush W^{20} and the interruption thereupon of the contact 912.

60 65 The closure of left-hand alternate contact

of RM^3 establishes circuit for the relay 2011 from ground, left-hand contact of RM^3 , contact 914 of the section, winding of 2011, negative battery to ground, which energizes, short-circuiting the winding of relay 2012, 70 which deenergizes, and upon the first step of the brushes of the manual incoming trunk selector from normal, places a short circuit around the winding of relay PT^{12} , which acts to prevent its energization. 75

The closure of contact 1 of 2011 connects ground with the contact 915 of the thousands section whereby, during the return of the brush W^{20} of the section, nine impulses of current are transmitted through the winding 80 of magnet PM^{12} from ground, contact 1 of 2011, contact 915 of the thousands section of the impulse transmitter, contact 4 of RC^{13} , contact 3 of 2009, brush W^{21} , its engaged passive contact 2007, alternate contact 4 of 1913, 85 contact 2 of SON^{12} , normal contact 4 of PT^{12} , winding of PM^{12} , negative battery to ground, which responds and rotates the brushes W^{74} to W^{74} , inclusive, step by step to the position with the brushes W^{74} to W^{74} , 90 inclusive, opposite the ninth row of passive contacts 1917 to 1919, inclusive, multiply connected terminals of trunk lines of the first minor group leading to and terminating in hundreds selector switches, to the passive 95 contacts of which are multiply connected selective terminals of final selector switches, to the passive contacts of which are multiply connected the called terminals of the lines of the fifth thousand group of substations. 100

The brush of the thousands section of the impulse transmitter continuing its return to normal, after the transmission of the impulses through its contact 915, following the disconnection of the brush from its fifth contact from normal, by the opening of contact 914 of the section, the circuit through the winding of relay 2011 is interrupted, the relay deenergized, its contacts opened, ground disconnected from the contact 915, and the short circuits removed from around the windings of relays 2012 and PT^{12} , whereupon circuit for the flow of current through the winding of relay PT^{12} is established from ground, left-hand alternate contact of PON^{12} , winding of PT^{12} , winding of coil 1923, negative battery to ground, which energizes the relay, disconnecting thereby the winding of coil 1923 from connection with relay 2012, whereby the relay 2012 is deenergized, and, if there be an idle trunk line 115 connected with a set of contacts of the row or group, establishes circuit for the relay ST^{12} , from ground, normal contact of the corresponding relay GBC^6 , contact 1920, brush W^{77} in engagement therewith, contact 3 of SON^{12} , contact 2 of PT^{12} , winding of ST^{12} , negative battery to ground, which energizes and establishes a vibratory circuit 120 for the magnet SM^{12} , whereby the brushes 125 130

W⁷⁴ to W⁷⁶ inclusive are rotated into connection with the first set of passive contacts 1917 to 1919, inclusive, of the row, multiply connected terminals of the first trunk line of the first minor group of the directively selected group.

Assuming, however, all trunks of the minor group connected with the ninth row of contacts 1917 to 1919, inclusive, to be busy, then the common relay GBC⁵ of such minor group will be energized, its normal contact opened and its alternate contact closed, with the result that upon the closure of contacts 3 and 4 of PT¹² a vibratory circuit for the magnet PM¹² is established from ground, alternate contact of GBC⁵, multiply connected group test passive contact 1921, brush W⁷⁸ in engagement therewith, contact 3 of PT¹², interrupter contact of PM¹², alternate contact 4 of PT¹², winding of PM¹², negative battery to ground, which is actuated and rotates the brushes W⁷⁷ to W⁷⁹, inclusive, out of connection with the group passive contacts 1920 to 1922, inclusive, respectively, of the ninth row or minor row to connection with the contacts 1920 to 1922, inclusive, corresponding to the tenth row of passive contacts 1917 to 1919, inclusive, multiply connected selective terminals of the last minor group of terminals connected with hundreds selectors of the fifth thousands group; whereupon, owing to the absence of ground connection with the passive contact 1921 of such minor group, circuit through the magnet PM¹² is interrupted, and, owing to direct ground connection with the passive contact 1920 of the row, circuit is established for the relay ST¹² from ground, contact 1920, brush W⁷⁷ in engagement therewith, contact 3 of SON¹², contact 2 of PT¹², winding of ST¹², negative battery to ground, which is energized; whereupon a vibratory circuit for the magnet SM¹² is established from ground, contact 3 of ST¹², interrupter contact and winding of SM¹², negative battery to ground, which responds and rotates the brushes W⁷⁴ to W⁷⁶, inclusive, into connection with their first set of contacts 1917 to 1919, inclusive, respectively, multiply connected terminals of the first trunk line of the selected minor group, during which movement of the brushes, if the first trunk line be idle, owing to the opening of the contact 3 of SON¹², circuit for the relay ST¹² is interrupted, the relay deenergized and the vibratory circuit through the winding of magnet SM¹² interrupted, preventing further rotation of the brushes in their selecting operation.

Assuming, however, the trunk line connected to the first set of contacts of the selected row to be busy, the engagement of brush W⁷⁴ with the contact 1919 thereof, prior to the opening of contact 3 of SON¹², establishes a holding circuit for the relay

ST¹² from ground, normal contact 4 of ST¹², brush W⁷⁶, its engaged passive contact 1919 of some other manual incoming trunk selector, local incoming trunk selector, (Fig. 11) or interoffice incoming trunk selector, (Fig. 15, Part 2), thence through contact 1919, brush W⁷⁶ in engagement therewith, alternate contact 4 of ST¹², alternate contact 4 of RR¹², winding of ST¹², negative battery to ground, which maintains the relay ST¹² in its energized position and the vibratory circuit for magnet SM¹² closed so long as the brushes W⁷⁴ to W⁷⁶ inclusive, pass into and out of connection with their associated sets of passive contacts of the row, multiple terminals of busy trunk lines. Upon the brush W⁷⁶ engaging a contact 1919 connected with a hundreds selector then idle, owing to the absence of ground connection with such contact, the circuit for the relay ST¹² is interrupted, the relay deenergized, and, by the opening of its contact 3, interrupts the vibratory circuit for the magnet SM¹², preventing its further actuation, leaving thereby the brushes W⁷⁴ to W⁷⁶, inclusive, in engagement with their contacts 1917 to 1919, inclusive, respectively, terminals of the then idle trunk line.

The closure of normal contact 4 of ST¹², responsive to its deenergization, connects ground through the brush W⁷⁶ to the contact 1919 of the selected trunk line, which acts to prevent the selection of such trunk line by any other incoming selector to the passive contacts of which the trunk line is connected.

Operation of hundreds selector in a connection between a manual and an automatic call distributing office.

Following the selection of a hundreds selector by the manual incoming trunk selector, a circuit is established for the flow of current through winding of relay 2012 and the right-hand winding of relay RR⁵ from ground, winding of 2012, alternate contact 1 of RC¹³, contact 4 of 2009, brush W⁸⁸, its engaged passive contact 2008, normal contact 1 of 1909, alternate contact 3 of 1915, alternate contact 3 of 1916, contact 2 of ST¹², brush W⁷⁵, its engaged passive contact 1918, normal contact 1 of PON⁵, right-hand winding of relay RR⁵, negative battery to ground, which are energized, and in respect to RR⁵, a holding circuit therefore is established from ground, normal contact 4 of ST¹², brush W⁷⁶, its engaged passive contact 1919, contact 2 and right-hand winding of RR⁵, negative battery to ground, which holds the relay in its energized position as long as the contact 4 of ST¹² remains closed. In respect to 2012, by the closure of its contact, an initial energizing circuit for the flow of current through the

winding of magnet RM³ of the hundreds section of the impulse transmitter is established from ground, contact 1 of 2013, contact of 2012, contact 918 of the thousands 5 section of the impulse transmitter, contact 3 of 924, normal contact and winding of RM³ of the hundreds section, negative battery to ground, which is energized, and in the manner described, interrupts its initial 10 energizing circuit, closes, through its right-hand alternate contact, its holding circuit and by the closure of its left-hand alternate contact connects ground with contact 914 of the section, and thence through the winding 15 of 2011, which is energized, and, in the manner described, short-circuits the winding of 2012, causing its deenergization, and thereafter upon the first step of the brushes of the hundreds selector from normal, 20 short-circuits the winding of the relay PT⁵.

The closure of contact 1 of 2011 connects ground with the contact 915 of the hundreds section of the impulse transmitter which, during the return of the brush of the 25 section to normal, transmits three impulses of current, through the winding of magnet PM⁵, which responds and in the manner described rotates the brushes of the hundreds selector to the third row of passive contacts 1201 to 1203, inclusive, multiply connected selective terminals of final selectors of the first minor group, of the second hundreds group, to the passive contacts of which are multiply connected the called 30 terminals of the substations of the third and fourth hundreds of the fifth thousands group.

Thereafter, the brush of the hundreds section of the impulse transmitter continuing 40 to return to normal, upon disconnection from its fifth contact from normal, by the opening of contact 914 of the section circuit through relay 2011 is interrupted, the relay deenergized, its contacts opened, ground 45 disconnected from contact 915 of the hundreds section, and the short circuit then existing around the windings of relays 2012 and PT⁵ removed, whereupon the relay PT⁵ is energized and an idle final selector selected in the manner previously described. 50

Operation of final selector in a connection between a manual and an automatic call distributing office.

55 Following the selection of a final selector, an energizing circuit is established for the flow of current through the winding of 2012 and the right-hand winding of RR⁶, which may be traced from ground, through 60 winding of 2012, thence over the previously traced path, through the hundreds selector, to the final selector, through the normal contact of PCN⁶ thereof, right-hand winding of RR⁶, negative battery to ground, energizing the relays, and in respect to RR⁶, a hold-

ing circuit therefor is established through the normal contact 4 of ST⁶, which holds the relay in its energized position during the closure of normal contact 4 of ST⁶, as previously described. 70

Following the return to normal of the hundreds section of the impulse transmitter, circuit for the flow of current through the winding of RM³ of the tens section of the impulse transmitter is established from 75 ground, thence over the previously traced path through contact 918 of the hundreds section, contact 1 of 2012, contact of 2012, contact 3 of 924, normal contact and winding of RM³ of the tens section, negative battery 80 to ground, which is energized; whereupon a holding circuit therefor is established from ground, contact 912 of the section, right-hand alternate contact and winding of RM³, negative battery to ground, the brush of the 85 section started on its return to normal and, by the closure of the left-hand alternate contact of RM³, circuit is established for the flow of current through winding of 2011, from ground, contact 914, thence through 90 winding of 2011, negative battery to ground, which energizes the relay, and, in the manner described, connects ground with the contact 915 of the tens section of the impulse transmitter, short-circuits the winding 95 of 2012, and upon the first step of the brushes of the final selector from normal, short-circuits the winding of PT⁶.

Thereafter, during the return to normal of the tens section of the impulse transmitter, four impulses of current are transmitted 100 from ground, through the contact 915 of the section, thence over the previously traced path through the hundreds selector and then, as previously described, through the 105 winding of PM⁶, which responds and rotates the brushes to the fourth row of passive contacts 1301 to 1304 inclusive.

Thereafter the brush of the tens section continuing to return to normal, upon disconnection from its fifth contact from normal, by the opening of contact 914, circuit for the flow of current through the winding of relay 2011 is interrupted, the relay deenergized, which disconnects ground from 110 the contact 915 of the tens section of the impulse transmitter, removes the short circuit from around the winding of relay 2012 and the then existing short circuit from around the winding of PT⁶, whereupon the relay 115 PT⁶ is energized over the hereinbefore described circuit, the magnet PM⁶ disconnected from the impulse transmitter, the relay ST⁶ connected with brush W⁴⁰, now in engagement with the grounded contact 1305 120 corresponding to the fourth row, which energizes the relay ST⁶ over a circuit from grounded contact 1305, brush W⁴⁰ in engagement therewith, contact 3 of PT⁶, upper 125 normal contact 2 and winding of ST⁶, nega- 130

tive battery to ground, establishing, by the closure of its alternate contact 2, its described holding circuit, and removes the short circuit from around the winding of 5 2012, whereupon the relay 2012 is energized, and upon the return to normal of the brush of the tens section of the impulse transmitter, by the closure of the contact 918 thereof, circuit for the magnet RM³ of the units section 10 is established from ground, contact 1 of 2013, contact of 2012, contact 918 of the tens section of the impulse transmitter, contact 3 of 924, normal contact and winding of RM³ of the units section of the impulse 15 transmitter, negative battery to ground. The magnet RM³ responding thereto, by the opening of its normal and closure of its right-hand alternate contact, interrupts its initial energizing circuit and establishes, 20 through contact 912 of the section, a holding circuit therefor, which holds the magnet in its energized position until the return to normal of the brush of the section, whereupon, by the opening of contact 912, the magnet RM³ and relay 924 of the section are 25 deenergized and returned to normal.

The closure of the left-hand alternate contact of RM³ establishes circuit, through contact 914 of the section, for the flow of current 30 through the winding of 2011, which is energized, its contacts closed, ground connected with the contact 915 of the units section, and the windings of relays 2013 and 1308 short-circuited.

Thereafter, during the return to normal of 35 the brush of the units section of the impulse transmitter, responsive to the closures and interruptions of its contact 915, six impulses of current are transmitted through the winding of SM⁶ from ground, contact 1 of 2011, contact 915 of the units section, thence over the previously traced path to contact 1 of ST⁶, normal contact of XT, winding of SM⁶, negative battery to ground, actuating the 40 magnet SM⁶, which rotates the brushes W³⁶ to W³⁵, inclusive, into connection with the associated sixth sets of passive contacts 1301 to 1304, inclusive, of the row.

Thereafter, when the brush of the units 45 section of the impulse transmitter, during its return to normal, passes out of connection with its fifth contact, by the opening of the contact 914, circuit through relay 2011 is interrupted, the relay deenergized, its contacts 50 opened, ground disconnected from the contact 915, and the described short circuit existing through contact 2 of 2011 around the windings of 2012 and 1308 removed; whereupon the relays 1308 and 2012 are energized 55 in multiple through the winding of coil 1312.

The energization of relay 1308 establishes 60 the energizing circuit for relay 1309, which responds, short-circuiting the upper left-hand and lower windings of XT, and establishes circuit for the flow of current through

the winding of 1307 from ground, contact of SON⁶, normal contact of BFR, contact 1 of 1309, winding of 1307, negative battery, to ground, which is energized, whereupon the described holding circuit therefor is established, which holds the relay in its energized position as long as the relay BFR 70 remains deenergized.

The opening of contact 4 of 1307 interrupts the then existing path for the flow of 75 current through the winding of relay 2012, whereby the relay is deenergized and its contact opened. The interruption of normal contact 3 of 1307 disconnects the magnet SM⁶ from the upper talking strand of the 80 trunk line. The closure of contact 1 of 1307 establishes circuit for the flow of current through the winding of relay LTR from ground, contact 2 of 1309, winding of LTR, contact 1 of 1307, brush W³⁵, its engaged 85 passive contact 1303, thence over the previously described path, through winding of relay CO, or CO² or CO³, negative battery, or positive battery to ground, whereby the relay CO, or CO², or CO³ is energized, its 90 contacts opened, disconnecting the relay LR, or LR², or LR³ from the line; and assuming the line to be idle, the flow of current is sufficient to energize the relay LTR to cause the opening of its normal and closure of its alternate contacts, whereupon, circuit for the flow 95 of current through the winding of CR⁶ is established from ground, contact of SON⁶, normal contact of BFR, contact 2 of LTR, winding of CR⁶, negative battery to ground, which is energized, its contacts closed, whereby the line of the called substation is extended to connection with the contacts of the ringing control relays 1915 and 1916, and by the closure of contact 3 of CR⁶ a short circuit 100 is placed around the left-hand winding of the upper coil and the winding of the lower coil of relay XT.

Restoration to normal of impulse transmitting apparatus. 110

Returning now to the units section of the impulse transmitter, upon the return to normal of its brush and the opening of its contact 912, the holding circuits for the relay 115 924 and magnet RM³ of the section are interrupted, which deenergize, whereupon, by the opening of normal contact 1 of 924, the circuit of relay 2013 is interrupted and the relay deenergized, which, by the opening 120 of its contact 4, interrupts the then existing holding circuits for the relay 2014 and for the magnet RM¹⁵ of the division of the recorder, whereupon the relay and magnet are deenergized, resulting, by the opening 125 of contact 1 of 2014, in the interruption of circuit for the flow of current through winding of relay 2009, which is deenergized, which, by the opening of its contact 1, interrupts the holding circuit for the relays 130 130

RC¹³ and 1913, which deenergize and in respect to RC¹³ establishes circuit for the flow of current through ST¹² from ground, normal contact of PT¹², contact of PON¹², normal contact 3 of RC¹³, alternate contact 1 of RR¹², winding of ST¹², negative battery to ground, which is energized, establishing, by the closure of its alternate contact 3, a vibratory circuit for the magnet SM¹², 5 which responds and rotates the brushes W⁸⁶ to W⁸⁸, inclusive, step by step to the position one step beyond the last set of passive contacts of the row; whereupon the brush W⁸⁴ is rotated to normal and the brushes 10 W⁸⁶ to W⁸⁸, inclusive, to the position above normal. Thereupon, by the opening of alternate contact of PON¹², the circuit for the relay ST¹² is interrupted, the relay deenergized, which, by the opening of its alternate contact 3, interrupts circuit for the 15 flow of current through the winding of magnet SM¹², preventing its further actuation. Also, by the opening of the alternate contact of PON¹², the holding circuits for the 20 relays RR¹² and 2010 are interrupted, the relays deenergized, which in respect to 2010, by the opening of its contact, interrupts the then existing circuit for the flow of current through the winding of relay 2012, 25 which deenergizes.

Simultaneously with the opening of the alternate contact of PON¹², the brushes W⁸⁵ to W⁸⁸ inclusive are rotated to normal position, whereupon the alternate contact of SON¹² is opened, its normal contact closed, and the switch placed in condition to be again allotted and actuated to select any trunk line of the associated group responsive to the actuation of the assignment key 40 thereof.

Operation of signaling a called subscriber.

Referring now to the deenergization of relay 1913, following the opening of contact 45 1 of 2009, as described, by the opening of its alternate contact 3, the interrupter I¹⁰ is disconnected from the lamp 1905, whereby its further flashing is prevented.

The closure of normal contact 4 of 1913 50 establishes circuit for the flow of current through the winding of relay 1914 from ground, normal contact of line relay LR, or LR², or LR³, through lamp LL, or LL², or lamps LL³, as the case may be, multiply 55 connected passive contact 1304, brush W³⁹ in engagement therewith, or from ground, alternate contact 1 of LTR, contact 3 of slow release relay 1309, at this time in its energized position, alternate contact 3 of 60 1307, upper talking strand of the trunk line, alternate contact 1 of 1916, contact 1 of 1915, normal contact 4 of 1913, normal contact 4 and winding of 1914, negative battery to ground, which is energized, establishing 65 its holding circuit from ground,

contact 1 of PON¹², alternate contact 4 and winding of 1914, negative battery to ground, which holds the relay in its energized position as long as contact 1 of PON¹² remains closed, and establishes circuit for 70 the flow of current through lamp 1905, from ground, alternate contact 3 of 1914, normal contact 3 of 1913, contact 2 of 1911 (now deenergized as a result of the opening of contact 2 of 1913) through lamp 1905, negative 75 battery to ground, which causes the lamp to burn steadily thereafter until disconnection. Also assuming the plug switch terminal at the manual exchange to have been connected with the multiple jack of 80 the trunk line, by the closure of alternate contact 3 of 1914, circuit for the flow of current through the upper winding of relay 1909 is established from ground, alternate contact 3 of 1914, contact 3 of 1910 85 (now energized), upper winding of 1909, negative battery to ground, which is energized, establishing its holding circuit from ground, contact 1 of PON¹², contact 3 and lower winding of 1909, negative battery to 90 ground, which holds the relay in its energized position as long as the contact 1 of PON¹² remains closed.

Also, assuming a plug switch to have been connected with the multiple jack of the 95 trunk line by the closure of contact 2 of 1914, circuit for the flow of current through the right-hand winding of 1915 is established from ground, contact of relay 1907, contact 2 of 1914, right-hand winding of 1915, negative 100 battery to ground, which deenergizes the relay and establishes circuit for the flow of signaling current over the line of the called substation, which may be traced from grounded ringing device (not shown), 105 passive contact 1922 multiply connected therewith, brush W⁷⁹ in engagement therewith, winding of GTR³, normal contact 3 of 1915, alternate contact 3 of 1916, contact 2 of ST¹², brush W⁷⁹, its engaged passive contact 1918, thence over the lower strand of the trunk lines and the line of the called substation, through the signaling apparatus thereof, to ground, or through the substation signaling apparatus to the upper 115 strand of the substation line to passive contact 1917, brush W³⁴ in engagement therewith, thence through alternate contact 1 of 1916, normal contact 2 of 1915, contact 3 of RR¹² to ground, whereby the signal or signals of the substation are actuated. 120

Thereafter, following the response of the called party, the relay GTR³ is, in the manner described, sufficiently energized to open its contact, which interrupts the holding circuit of the relay 1916, which deenergizes, interrupting, by the opening of its alternate contacts 1 and 3, the connection of signaling current with the line, and by the closure of its normal contacts 1 and 3 connects the 130

right-hand windings of the repeating coil 1906, relay 1908 and negative battery with the called substation; whereupon the relay 1908 is energized, its contact closed, the 5 right-hand high resistance winding of relay 1907 short-circuited, which increases the flow of current over the manual incoming trunk line, through the supervisory apparatus at the manual office, to an extent sufficient 10 to cause its actuation and indicate to the operator at the manual office that the party at the called substation has answered.

Restoration of connection.

15 After the completion of the conversation, responsive to the "hanging up" at the substation, the circuit for the flow of current through the winding of relay 1908 and right-hand windings of the repeating coil 20 1906 is interrupted, the relay 1908 deenergized, its contact opened, and the short-circuit from around the winding of 1907 removed, with the result that the flow of current over the manual incoming trunk line is 25 sufficiently decreased to actuate the supervisory apparatus of the connecting circuit at the manual exchange in a manner to signal the operator thereat that the party at the called substation has "hung up."

30 Thereafter, responsive to the actuation of the disconnect signal associated with the line of the calling substation, the operator at the manual office disconnects the plug switch from the multiple jack of the manual incoming trunk line, whereupon circuit for the flow of current through the relay 1907 is 35 interrupted, the relay deenergized, its contact opened, interrupting thereby the then existing circuit for the flow of current 40 through the lower winding of relay 1910 and the right-hand winding of 1915, which, in respect to the relay 1915, causes, owing to the flow of current through its left-hand winding through contact 3 of RR¹², the energization 45 of the relay, and establishes circuit as hereinbefore described for the relay 1916.

Responsive to the interruption of circuit for the flow of current through the lower winding of relay 1910 when the brushes of interrupter I¹² pass out of connection with their live segments, the relay is deenergized, which, by the opening of its alternate contact 3, interrupts the existing holding circuit for the relay RR¹² and establishes therefore, through normal contact 4 of 1910, a substitute holding circuit through the interrupter I¹², with the result that when the brushes of I¹² pass out of connection with 55 their live segments, circuit for the flow of current through relay RR¹² is interrupted, the relay deenergized, whereupon, by the interruption of its contact 3, circuit for the flow of current through the right-hand 60 winding of relay 1915 and through the

winding of relay 1916 is interrupted, which deenergize.

The closure of normal contact 4 of RR¹², upon its deenergization, establishes circuit for the flow of current through ST¹² from 70 ground, contact 1 of PON¹², normal contact 4 of RR¹², winding of ST¹², negative battery to ground, which energizes, establishing the vibratory circuit for the magnet SM¹², which rotates the brushes W⁷⁴ 75 to W⁷⁶, inclusive, step by step into and out of connection with their remaining sets of contacts of the row, until the brushes reach the position two steps above the last set of contacts, whereupon the brushes W⁷⁷ to W⁷⁹, 80 inclusive, are rotated to normal position, and the brushes W⁷⁴ to W⁷⁶, inclusive, to the position above normal, when, by the opening of contact 1 of PON¹², the energizing circuit for the flow of current through 85 relays ST¹², 1909 and 1914 is interrupted, the relays deenergized, and, in respect to relay ST¹², by the opening of its contact 3, the vibratory circuit through magnet SM¹² is interrupted, whereby its further actuation 90 is prevented.

When the brushes W⁷⁷ to W⁷⁹, inclusive, reach normal position, in addition to the opening of alternate contacts of PON¹², the brushes W⁷⁴ to W⁷⁶ are rotated to normal 95 position, whereupon the alternate contact of SON¹² is opened and the normal contacts thereof closed.

The deenergization of relay 1914 interrupts the flow of current then existing 100 through the lamp 1905, which is extinguished and, as a result of the deenergization of relays 1909 and 1914, circuit for the flow of current through 1904, established after the deenergization of relay 1910 105 through its normal contact, is interrupted, extinguishing thereby the lamps, and thus placing the manual incoming trunk line and the manual incoming trunk selector thereof in condition to be assigned and utilized in establishing some other connection. 110

Responsive to the energization of relay ST¹² by the opening of its normal contact 4, the holding circuit through relay RR⁵ is 115 interrupted and the relay deenergized, following which the selector is restored to normal, during which, by the opening of contact 4 of ST⁵, the holding circuit for relay RR⁶ is interrupted, the relay deenergized and the final selector restored, as hereinbefore described. 120

Busy condition of all available paths to called substation.

Should, during the attempted connection 125 with a line, all hundreds selectors of the desired group multiply connected with the passive contacts of a manual incoming trunk selector be in use, then the brushes W⁷⁴ to W⁷⁶, inclusive, will be rotated step 130

by step into and out of connection with the sets of passive contacts of the last row or minor group of the selected group to the position one step beyond the last set of the row and the contacts of SOR¹² closed, or if all final selectors of a desired group be, at the time of attempted selection, busy, then the brushes W⁸¹ to W⁸⁸, inclusive, will be rotated into and out of connection with all of the contacts of the last row or minor group of a selected group, to the position one step beyond the last set of contacts, and the contacts of SOR⁸ closed, with the result that upon the closure of contact 963 of the tens section of the impulse transmitter; that is, during the travel of the brush of the section from positions 4 to 3 inclusive, circuit is established for the flow of current through the left-hand winding of relay 965 from ground, left-hand contact of SOR⁸, passive contact 1917, brush W⁸⁴ in engagement therewith, contact 1 of ST¹², alternate contact 1 of 1916, alternate contact 1 of 1915 or right-hand contact of SOR¹², alternate contact 4 of 1913, passive contact 2007, brush W⁸⁷ in engagement therewith, contact 3 of 2009, contact 4 of RC¹³, contact 963 of the tens section of the impulse transmitter, left-hand winding of 965, negative battery to ground, which is energized and holding circuit established therefor from ground, contact 912 of the units section, right-hand contact and winding of 965, negative battery to ground, which holds the relay in its energized position until the return to normal of the brush of the units section and the interruption thereupon of the contact 912 of the section.

Thereafter, during the return to normal of the brush of the units section of the impulse transmitter, upon engaging its fourth contact from normal, a short circuit is placed around the winding of relay 1913, from ground, left-hand contact of 965, contact of 964 (closed from positions 4 to 3 inclusive), contact 1 of 2009, alternate contact 2 of RR¹², thence over the previously traced path to one terminal of the winding of relay 1913, the other terminal of which is connected with ground, as a result of which the relay 1913 is deenergized and, in the manner described, establishes an initial energizing circuit for the relay 1914.

Thereafter, during the continued return to normal of the brush of the units section of the impulse transmitter, upon passing out of connection with its third contact, by the opening of contact 964, the traced short circuit is removed from around the winding of relay 1913, which is again energized over the previously traced path in series with the winding of relay RC¹³, whereupon circuit is established for the flow of current through the winding of relay 1911 from ground, al-

ternate contact 3 of 1914, contact 2 of 1913, winding of 1911, negative battery to ground, which is energized, establishing a holding circuit therefor from ground, alternate contact 4 of 1910, alternate contact 4 of 1909, right-hand contact of key 1903, normal contact of key 1902, alternate contact 3 and winding of 1911, negative battery to ground, disconnects the interrupter I¹⁰ from lamp 1905 and connects the interrupter I⁹ with the lamp 1904, whereby, responsive to each closure of the brushes of the interrupter I⁹ with its live segments, a circuit for the flow of current through the lamp 1904 is established, which causes the lamp to flash in a distinctive manner and indicates to the operator that all available paths to the line of the called substation are unselectable.

The opening of normal contact 3 of 1911 interrupts the holding circuit through the left-hand winding of relay RR¹², whereby the relay is deenergized and the restoring circuits for the manual incoming trunk selector established, whereupon the selector is restored to normal, following which, if selected, the restoring circuits of the hundreds selector are established and the selector restored, as heretofore described.

Function of disconnect key 1903.

After the assignment of a trunk and the actuation of its assignment key 1909, the operator by actuation from normal of the disconnect key 1903, will cause disconnection and restoration of any actuated apparatus then operatively associated with such trunk lines. Thus, should a connecting circuit finder be in connection with the trunk line at the time of actuation of the key 1903, the described holding circuit through the left-hand contact thereof, for the relay RC¹³, will be interrupted, the relay deenergized, the restoring circuits for the finder established, and the finder, in the manner described, restored to its normal position. Also assuming the recording keys, recorder and impulse transmitter to have been actuated, the relays 2010 to 2014 inclusive energized and deenergized as before described, and an energizing circuit established for the relay 2012, which in this case may be traced from ground, winding of 2012, normal contact 1 of RC¹³, contact 2 of 2010, winding of coil 2115; negative battery to ground, the restoring circuits for the impulse transmitter will be established and result in its restoration to normal.

Assuming, at the time of actuation of key 1903 of a manual incoming trunk circuit, the relay RR¹² and the described holding circuit therefor through its contact 2, to have been established, then, by the opening of the right-hand contact of key 1903, such holding circuit will be interrupted, the relay RR¹²

deenergized, following which the previously described restoring circuits for the manual incoming trunk selector will be established, and, if actuated, the restoring circuits established for the hundreds selector and final selector, whereupon such selectors will, in the manner described, be restored to their normal positions, and placed in condition to be utilized in establishing other connections.

10 *Successive operation of two assignment keys 1901.*

Should the operator at the automatic call distributing office, after actuation of the assignment key 1901 and before the numerical designation of the called substation has been recorded, as a result of the actuation of the recording keys, actuate from normal the assignment key 1901 of another manual incoming trunk line of the group, then by the closure of the left-hand contact of the second actuated assignment key, circuit from ground therethrough for the common relay 2001 will be established, the relay energized, its contact opened and as a result the holding circuit then existing for the relay RC^{13} of the finder will be interrupted, the relay deenergized and the restoring circuits for the manual incoming trunk finder, in the manner described, established, whereupon the finder will restore to normal and be placed in a condition to be used, when allotted, in the establishment of another connection.

35 Responsive to the closure of right-hand contact of the second actuated key 1901, the previously described circuits for causing the actuation of a manual incoming trunk finder will be, in the manner described, established, and the connection of such manual incoming trunk finder with the trunk line of the second actuated key effected, whereupon, responsive to the actuation of the recording keys corresponding to the numerical designation of the desired called substation, the apparatus will be actuated to establish connection of such called substation with the manual incoming trunk line.

50 *Function of holding key 1902.*

As stated, each manual incoming trunk circuit is provided with a holding key 1902, which, when actuated from normal, will interrupt the previously described holding circuit for relay RR^{12} , and, by the closure of its alternate contact, establish a substitute holding circuit therefor from ground, alternate contact of 1902, normal contact 3 of 1911, contact 2 and left-hand winding of RR^{12} , negative battery to ground, which will prevent its deenergization as long as the key 1902 remains in its off-normal actuated position, whereby the establishment of the restoring circuits for the manual incoming trunk selector and, if selected and actuated,

the restoring circuits for the hundreds selector and final selector, will be prevented.

Operation of re-ringing a called subscriber.

After the establishment of connection 70 with a called substation over a manual incoming trunk line, should it be desired to recall the party at the called substation, the operator at the manual office will remove the calling plug switch from connection with 75 the multiple jack terminal of the trunk line, interrupting circuit for the flow of current through the windings of relay 1907, which will deenergize, open its contact, and interrupt circuit for the flow of current through the lower winding of 1910 and through the right-hand winding of relay 1915, whereupon the relay 1915, owing to the then existing flow of current through its left-hand winding, will be energized and, in the manner described, establish the energizing circuit for the relay 1916. Thereafter the operator at the manual office in a predetermined time (for example—two seconds or less) again establishes connection of the calling on plug switch with the multiple jack terminal of the trunk line, establishing circuit for the flow of current through windings of 1907, which energize, closes its contact and reestablishes circuit for the flow of current 80 through the lower winding of relay 1910 and right-hand winding of relay 1915, which, assuming the brushes of the interrupter J^{14} to have passed out of connection with their live segments, reenergizes the relay 1910 and deenergizes the relay 1915; whereupon circuit for the flow of signaling current over the line of the called substation is, as described, reestablished to actuate the signaling apparatus of the substation. Thereafter, following the response at the called substation, the conversational circuit between the calling and called substations, as a result of the deenergization of relay 1916 and the closure of its normal contacts, is reestablished. Thereafter, when the calling and called subscribers "hang up," the disconnect signals are displayed before the operator at the manual office and, responsive to disconnection of the plug switches from the jack of the line of 105 the calling substation and the jack of the trunk line, the apparatus will be restored to normal in the manner previously described.

110 What is claimed is:

1. In a telephone exchange system: a line selector switch, a plurality of lines terminating thereon, a connecting circuit selector switch individual to said line switch, a plurality of groups of connecting circuits terminating thereon and extending to a plurality of operators, means for simultaneously starting said line and connecting circuit switches, and means including said switches for extending a line to an idle connecting circuit 120 125 130

- in a group leading only to an operator then idle.
2. In a telephone exchange system, a line selector switch, a plurality of lines terminating thereon, a connecting circuit selector switch individual to said line switch, a plurality of connecting circuits terminating thereon and extending to a plurality of operators, means for simultaneously starting said line and connecting circuit switches, and means including said switches for extending a line to an idle connecting circuit leading only to an operator then idle. 65
3. In a telephone exchange system, a plurality of line and connecting circuit selector switches connected in pairs, each of said switches being provided with a plurality of sets of passive contacts and a set of coöperating contact brushes, subscribers' lines multiply connected to the passive contacts of said line switches, connecting circuits multiply connected to the passive contacts of said connecting circuit switches and leading to a plurality of operators, means for simultaneously starting the contact brushes of an idle pair of said switches, and means including said switches for extending a line to an idle connecting circuit leading only to an operator then idle. 70
4. In combination with a selector switch, operators' positions, a plurality of groups of connecting circuits, each said group comprising a plurality of said circuits terminating at one end in said switch and at the other 75
- end in one of said operators' positions, secondary selector switches, a plurality of link circuits each terminating at one end in said selector switch and at the other end in one of said secondary selector switches, a second plurality of groups of connecting circuits, each said group comprising a plurality of said circuits terminating at one end in said secondary selector switches and at the other end in a different one of said operators' positions, of means for starting said selector switch to seek first a group leading to a position under control of an idle operator, second, to seek an idle circuit in such group and third, upon failure to select a group leading to an idle operator, to select an idle one of said link circuits, and means thereupon actuated to cause the secondary selector switch in which said selected link circuit terminates to seek first a group of connecting circuits leading to an operator then idle in said second plurality of groups of connecting circuits and second to seek an idle circuit in such group. 80
5. In a telephone exchange system, a line selector switch, a plurality of lines terminating thereon, a connecting circuit selector switch individual to said line selector, a plurality of connecting circuits terminating on said connecting circuit selector and extend- 85
- ing to a group of operators, secondary connecting circuit selector switches, a plurality of link circuits each terminating at one end on said connecting circuit selector and at the other end in one of said secondary selectors, a plurality of connecting circuits multiply connected to said secondary selectors and leading to a second group of operators, means for simultaneously starting said line and connecting circuit selectors to select and connect a calling line with a connecting circuit leading to an idle operator of said first group, means operated in case no selectable circuit is found for causing said connecting circuit selector to select an idle secondary selector, and means thereupon actuated to cause the last said switch to select an idle connecting circuit leading to an idle operator of said second group and connect said line therewith. 90
6. In a telephone exchange system, a plurality of line and connecting circuit selector switches connected in pairs, each said switch provided with a plurality of sets of passive contacts and a set of coöperating contact brushes, subscribers' lines multiply connected to the passive contacts of said line switches, connecting circuits multiply connected to certain of the sets of passive contacts of said connecting circuit switches and leading to a group of operators, secondary connecting circuit selector switches provided with a plurality of sets of passive contacts and a set of coöperating contact brushes, connecting circuits multiply connected to the passive contacts of said secondary selectors and leading to a second group of operators, link circuits multiply connected to sets of passive contacts of said connecting circuit selectors each terminating in one of said secondary connecting circuit selectors, means for simultaneously starting the contact brushes of an idle pair of line and connecting circuit switches to select a calling line and an idle connecting circuit leading to an operator then idle, means operated in case no selectable connecting circuit is found for causing said connecting circuit selector to select an idle secondary selector, and means thereupon actuated to cause the contact brushes of the last said switch to seek an idle connecting circuit leading to an idle operator of said second group. 95
7. In a telephone exchange system, a central office switching station, lines terminating thereat, a plurality of subscribers' stations connected to certain of said lines, a connecting circuit at said central office, switching mechanisms at said central office for automatically connecting a calling line 100 with said connecting circuit, other mechanisms at said central office for completing connections between calling and called sub- 105
- 110
- 115
- 120
- 125

scribers' stations, and means operated in response to the extension of a calling line to the same line for automatically rendering said first mechanisms again selectable.

5 8. In a telephone exchange system, a central office switching station, lines terminating thereat, a plurality of subscribers' stations connected with certain of said lines, a connecting circuit at said central office, automatic switching mechanisms at said central office for connecting a calling line with said connecting circuit, other mechanisms at said central office for completing connections between calling and called subscribers' 10 stations, means operative in response to the extension of a calling line to the same line for automatically rendering said first mechanisms again selectable, together with means for preventing selection of said circuit by 15 said first mechanisms during connections of 20 said other mechanisms with said circuit.

9. In a telephone exchange system, a central office switching station, lines terminating thereat, a plurality of subscribers' stations connected to certain of said lines, a connecting circuit at said central office, automatic switching mechanisms at said central office for connecting a calling line with said connecting circuit, other mechanisms at said 25 central office for completing connections between calling and called subscribers' stations, and means operated in response to the extension of a calling line to the same line for automatically releasing said first mechanisms, a signal associated with said selected connecting circuit for indicating the existence of a reverte call, and means also responsive to the extension of a calling line to the 30 same line for displaying in a characteristic manner said signal.

40 10. In a telephone exchange system, a central office switching station, lines terminating thereat, a plurality of subscribers' stations connected with certain of said lines, a connecting circuit at said central office, automatic switching mechanisms at said central office for connecting a calling line with said connecting circuit, other mechanisms at said central office for completing connections between calling and called 45 subscribers' stations, means operative in response to the extension of a calling line to the same line for automatically releasing said first mechanisms, a signal individual to said connecting circuit for indicating the 50 existence of a reverte call, means also responsive to the extension of a calling line to the same line for displaying said signal, and means operated during connection of said other mechanisms with said connecting 55 circuit for preventing its selection by said 60 automatic mechanisms.

11. In a telephone exchange system, a central office switching station, lines terminating thereat, a plurality of subscribers' 65 stations connected to certain of said lines, a

plurality of connecting circuits at said central office, switching mechanisms at said central office for automatically connecting a calling line with an idle one of said connecting circuits, other mechanisms at said central office for completing connections between calling and called subscribers' stations, and means operated in response to the extension of a calling line to the same line for automatically rendering said first mechanisms again selectable. 70 75

12. In a telephone exchange system, a central office switching station, lines terminating thereat, a plurality of subscribers' stations connected to certain of said lines, a plurality of connecting circuits at said central office, automatic switching mechanisms at said central office adapted to connect a calling line with an idle connecting circuit extending only to an operator then 80 idle, other switching mechanisms at said central office for completing connections between calling and called subscribers' stations, and means operated in response to the extension of a calling line to the same line for automatically releasing said first mechanisms, a signal associated with said selected connecting circuit for indicating the existence of a reverte call, and means also responsive to the extension of a calling line to the 85 same line for displaying in a characteristic manner said signal.

13. In a telephone exchange system, a central office switching station, lines terminating thereat, a plurality of subscribers' stations connected to certain of said lines, a connecting circuit at said central office, switching mechanisms at said central office adapted to automatically connect a calling line with said connecting circuit, other 100 switching mechanisms at said central office for completing connections between calling and called subscribers' stations, and means operated in response to the extension of a calling line to the same line for automatically rendering said first mechanisms again 105 selectable and means for thereafter signaling the called subscriber's station. 110

14. In a telephone exchange system, a central office switching station, lines terminating thereat, a plurality of subscribers' stations connected to certain of said lines, a connecting circuit at said central office, automatic switching mechanisms at said central office for connecting a calling line with said 115 connecting circuit, other mechanisms at said central office for completing connections between calling and called subscribers' stations, and means operated in response to the extension of a calling line to the same 120 line for automatically releasing said first mechanisms, a signal associated with said connecting circuit, means also responsive to the extension of a calling line to the same 125 line for displaying said signal and means 130

for thereafter signaling the called subscriber's station.

15. In a telephone exchange system, a central switching station, subscribers' lines terminating thereat, selective switches for interconnecting said lines, a connecting circuit for coöperating with said switches in the establishment of a connection, means included in the circuits of said switches for automatically connecting signaling current to a called subscriber's line, additional means individual to said connecting circuit for coöperating with said means for reconnecting signaling current to a called subscriber's line, a signal individual to said connecting circuit, and means for displaying said signal during a signaling and a resignaling operation.

16. In a telephone exchange system, a
20 central switching station, subscribers' lines
terminating thereat, a connecting circuit
including a ringing signal individual there-
to, selective switches for interconnecting a
calling subscriber's line to said connecting
25 circuit, means for connecting called sub-
scribers' lines with said connecting circuit,
means for connecting signaling current with
a connected called subscriber's line, and
means for displaying said signal at all times
30 only during connection of said signaling
current with a called subscriber's line.

17. In a telephone exchange system, a central switching station, subscribers' lines terminating thereat, a connecting circuit 35 comprising a key, switching mechanisms, a calling subscriber's line connected with said connecting circuit in response to actuation of said switching mechanisms, means responsive to actuation of said key for disconnecting said line from said circuit, together with means for holding said mechanisms in their actuated positions.

18. In a telephone exchange system, a central switching station, subscribers' lines terminating thereat, a connecting circuit comprising a key, switching mechanisms, a calling subscriber's line and a called subscriber's line connected to said connecting circuit in response to actuation of said switching mechanisms, means responsive to actuation of said key for disconnecting said calling line from said circuit, together with means for holding said mechanisms in their actuated positions.

55 19. In a telephone exchange system, a central switching station, subscribers' lines terminating thereat, a connecting circuit comprising a key, switching mechanisms, a calling subscriber's line connected with said 60 connecting circuit in response to actuation of said switching mechanisms, means responsive to actuation of said key for disconnecting said line from said connecting circuit, together with means for 65 holding said mechanisms in their actu-

ated positions, and means thereafter responsive to restoration of said key for restoring said line to connection with said circuit.

20. In a telephone exchange system, a central switching station, subscribers' lines terminating thereat, a connecting circuit comprising a key, switching mechanisms, a calling subscriber's line connected with said circuit in response to actuation of said switching mechanisms, means responsive to actuation of said key for disconnecting said line from said circuit, together with means for holding said mechanisms in their actuated positions, and means for rendering said circuit unselectable during actuation of said key. 70 75 80

21. In a telephone exchange system, a central switching station, subscribers' lines terminating therewith, a plurality of connecting circuits each comprising a key individual thereto, switching mechanisms adapted upon actuation to connect a calling subscriber's line with an idle one of said circuits, means responsive to actuation of said key for disconnecting said line from said selected circuit, together with means for holding said actuated mechanisms in their actuated positions, and means during actuation of said key for rendering said selected circuit unselectable. 95 85 90 95

22. In a telephone exchange system including subscribers' lines, a plurality of connecting circuits each comprising a listening-in key, an operator's telephone, means for connecting said lines with said circuits, means actuated responsive to connection of a line with one of said circuits to automatically connect said telephone with said line, means for interrupting said automatic connection upon actuation of the listening-in key of another one of said circuits, together with means for thereafter reestablishing said automatic connection upon restoration of said key. 100 105

23. In a telephone exchange system, a central switching station, subscribers' lines terminating thereat, a plurality of connecting circuits each provided with a listening-in key appearing at an operator's position, an operator's telephone common to said circuits, means for connecting said lines with said circuits, means actuated upon connection of a line with an idle one of said circuits to automatically connect said telephone with said line, means responsive to actuation of the listening-in key of any other one of said circuits for interrupting said automatic connection, and means thereafter actuated upon restoration of said key to restore said automatic connection. 110 115 120 125

24. In a telephone exchange system including subscribers' lines, a plurality of connecting circuits each comprising a listening-in key, an operator's telephone, means for automatically connecting said lines with 130

- said circuits and with said telephone, means actuated responsive to actuation of the listening-in key of one of said circuits to interrupt the automatic connection of said telephone with another said circuit, together with means for preventing the connection of any line with any of said circuits during said actuation, and means actuated responsive to restoration of said key to reestablish 10 said automatic connection.
25. In a telephone exchange system comprising subscribers' lines, an indicating signal individual to each of said lines, a connecting circuit comprising a listening-in key, 15 means for temporarily connecting any one of said lines with said circuit, means for causing display of the signal of said connected line, and means responsive to an actuation of said key for effacing said signal.
20. 26. In a telephone exchange system comprising subscriber's lines, a central switching station, a signal individual to each of said lines at said station, a plurality of connecting circuits each comprising a listening-in key, means for extending said lines when calling to connection with said circuits, means common to said circuits effective upon actuation of the said key of any one of said circuits to cause display of the signal of any 30 one of said lines connected with said circuit.
27. In a telephone exchange system comprising subscribers' lines, a central switching station, a signal for each line at said station, a plurality of connecting circuits each 35 comprising a listening-in key, a key common to said circuits, means for extending said lines when calling to connection with said circuits, means operated responsive to actuation of the listening-in key of any one of 40 said circuits to render said common key, when actuated, effective to cause display of the signal of a connected line.
28. In a telephone exchange system including subscribers' lines, an indicating signal for each of said lines, a plurality of operators' positions, a plurality of connecting circuits associated with each of said positions and each comprising a listening-in key, a key individual to each said position 50 and common to the connecting circuits thereof, means for effecting connection of any one of said lines with any one of said circuits, together with means for causing display of the signal of a connected line only 55 during the simultaneous actuation of the listening-in key and the common key of the associated connecting circuit.
29. In a telephone exchange system including subscribers' lines, an indicating signal 60 individual to each of said lines, a plurality of operators' positions each comprising a plurality of connecting circuits, a listening-in key individual to each of said circuits, a key individual to each position and 65 common to the said circuits thereof, means
- during connection of any one of said lines with any one of said circuits for displaying the said signal of said line connected therewith, together with means during such a connection for effacing said displayed signal 70 in response to an actuation of either one of the associated said keys.
30. In a telephone exchange system including subscribers' lines, a connecting circuit comprising a listening-in key, a disconnect key, a calling line and a called line connected with said circuit, means responsive to simultaneous operation of said keys to cause disconnection of said called line. 75
31. In a telephone exchange system including subscribers' lines, a plurality of connecting circuits each comprising a listening-in key, a disconnect key common to said circuits, selective switching mechanisms, one of said lines as a called line connected with 80 one of said circuits through said mechanisms, means responsive to the simultaneous actuation of the listening-in key of said connected circuit and said disconnect key for causing disconnection of said connected line 85 and for causing restoration of said mechanisms.
32. In a telephone exchange system including subscribers lines, a connecting circuit comprising a listening-in key, a disconnect key, selective switching mechanisms, a calling one of said lines connected with said circuit responsive to actuation of certain of said mechanisms, a called one of said lines connected with said circuit responsive to 90 actuation of certain other of said mechanisms, means responsive during simultaneous actuation of said keys to interrupt said connection of said called line, together with means for causing restoration of last said 95 mechanisms.
33. In a telephone exchange system including subscribers' lines, a plurality of connecting circuits each comprising a listening-in key, a disconnect key common to said circuits, selective switching mechanisms, one of said lines as a called line connected with one of said circuits through said mechanisms, means responsive to simultaneous actuation of the listening-in key of said connecting circuit and said disconnect key for causing disconnection of said connected line and for causing restoration of said mechanisms, and means operative during the simultaneous operation of two or more of said listening-in 100 keys for preventing said disconnection and 105 said restoration.
34. In a telephone exchange system including subscribers' lines, a connecting circuit comprising a listening-in key, a disconnect key, automatically actuated selective mechanisms, a called one of said lines connected with said circuit through said mechanisms, means responsive to the simultaneous actuation of said keys to cause interruption 110 115 120 125 130

of said connection and to cause restoration of said mechanisms.

35. In a telephone exchange system, a two-movement selector switch arranged to automatically hunt for a group of contacts connected to circuits leading to an idle operator in its primary movement and to automatically hunt for an idle one of said circuits in its secondary movement, a secondary selector switch, means for causing said first selector switch to seize said secondary selector switch upon the failure of said first selector switch to find a group of contacts connected to circuits leading to an idle operator, and means thereupon operated to cause said secondary selector switch to automatically hunt for a group of contacts connected to circuits leading to an idle operator in its primary movement and to automatically hunt for an idle one of said circuits in its secondary movement.

36. In a telephone exchange system, a central switching station, lines terminating therat, a plurality of subscribers' stations connected to certain of said lines, a connecting circuit at said central office, an automatic switch for finding a calling line, an automatic switch for extending said calling line from said line finder switch to said connecting circuit, other automatic switches in said central office for completing connections between calling and called subscribers' substations, and means operated in response to the extension of a calling line to the same line for automatically releasing said line finder switch and said connecting circuit selector switch and rendering them again selectable.

37. A set of recording keys, an impulse transmitter, means for temporarily operatively associating said transmitter with said keys, means including an actuation of any one of said keys for causing said transmitter to assume a position corresponding to the key actuated, and means for thereafter causing the transmitter to transmit impulses in accordance with the key actuated.

38. A plurality of sets of recording keys, a series of impulse transmitters, one or more for each set of said keys, means for temporarily operatively associating said transmitters with the said sets of keys, means responsive to the actuation of any one of the keys in each of the said sets for causing the said transmitters to assume positions corresponding to the actuated keys, and means for thereafter causing said transmitters to successively transmit impulses corresponding to said actuated keys.

39. A plurality of sets of recording keys, a series of one or more impulse transmitters for each set of said keys, means for temporarily operatively associating said transmitters with said keys, means responsive to actuation of any key in each said set for

causing the said transmitters to assume positions corresponding to the actuated keys, together with means for thereupon interrupting said operative association, and means for thereafter causing said transmitters to successively transmit impulses corresponding to said actuated keys.

40. A plurality of sets of recording keys, a plurality of series of impulse transmitters, each of said series comprising one or more of said transmitters for each said set of keys; means for temporarily operatively associating any one of said series with said sets of keys, means responsive to actuation of any key in each said set for causing the actuation of an operatively associated one of said series of transmitters to assume positions corresponding to the keys actuated, together with means for thereupon causing interruption of said operative association, and means for thereafter causing said operatively associated transmitters to successively transmit impulses in accordance with the keys actuated.

41. A plurality of sets of recording keys, a plurality of series of impulse transmitters, each said series comprising one or more of said transmitters for each of said sets of keys, means for successively temporarily operatively associating each said series with said sets of keys, means responsive to actuation of any key in each set for causing actuation of an operatively associated one of said series to assume positions corresponding to the keys actuated, together with means for thereupon causing interruption of the operative association of the actuated series with said keys, and means for causing operative association of another one of said series with said keys, together with means for thereafter causing said actuated transmitters to transmit successively impulses corresponding to the said actuated keys.

42. In a telephone exchange system, the combination with subscribers' lines, a plurality of connecting circuits divided into groups, a selector switch, a series of impulse transmitters associated with said switch, of means for connecting a line with an idle one of said connecting circuits in any one of said groups, means responsive to such connection for actuating the relay of the group including said connecting circuit, means for thereupon causing said switch to select said connected circuit and connect said transmitters therewith, and means effective during actuation of said relay for preventing connection of a calling one of said lines with any one of said connecting circuits.

43. In a telephone exchange system, the combination with subscribers' lines, a plurality of connecting circuits divided into groups, a relay associated with each of said groups, a plurality of selecting switches, a series of impulse transmitters associated

with each of said switches, of means for connecting a line with an idle one of said connecting circuits, means responsive to said connection for actuating the relay of the 5 group including said connecting circuit, means for thereupon causing an idle one of said switches to select said connected circuit and connect the associated series of said transmitters therewith, and means effective 10 during actuation of said relay for preventing connection of a calling one of said lines with any one of said connecting circuits.

44. In a telephone exchange system, the combination with subscribers' lines, a plurality 15 of connecting circuits divided into groups, a relay for each of said groups, a selector switch, of means for connecting a line with an idle one of said connecting circuits in any one of said groups, means responsive 20 to such connection for actuating the relay of the group including said connecting circuit, means for thereupon causing said switch to select first the group corresponding to said actuated relay, and to 25 then select said connected circuit, and means effective during actuation of said relay for preventing connection of a calling one of said lines with any one of said connecting circuits.

30 45. In a telephone exchange system, calling subscribers' lines, a plurality of connecting circuits, means for causing connection of said lines with said connecting circuits, a plurality of selector switches adapted 35 to select said connecting circuits, and means effective during the simultaneous actuation of all of said switches for preventing connection of any calling line with any one of said connecting circuits.

40 46. In a telephone exchange system including subscribers' lines, a plurality of connecting circuits, means for causing connection of said lines with said connecting circuits, a plurality of selector switches adapted 45 to select said connecting circuits, a relay common to said switches, means responsive during the simultaneous actuation of all of said switches for causing actuation of said relay, and means effective during actuation 50 of said relay for preventing connection of any calling line with any one of said connecting circuits.

47. The combination with a selector, a relay adapted to be actuated when connected 55 with a source of current of either plus or minus polarity, a motor magnet, a signaling device, of means effective upon actuation of said relay when connected with current of one of said polarities for causing the actuation of said magnet, and means effective 60 upon actuation of said relay when connected with current of the other said polarity to render effective the said signaling device.

48. The combination with a selector, a 65 relay having a normal and two actuated po-

sitions, said relay being responsive to current of one polarity to move its armature to one actuated position and responsive to current of the other polarity to move its armature to the other actuated position, a 70 motor magnet, a signaling device, of means effective in the normal position of said relay for causing the directive actuation of said magnet, means effective upon actuation of said relay when connected with current of 75 one polarity for causing the automatic actuation of said magnet, and means effective upon actuation of said relay with current of the other polarity to render effective said signaling device. 80

49. The combination with a selector, a relay, a test circuit, a motor magnet circuit, a restoring circuit, a signaling device, one winding of said relay adapted to be included in said test circuit, another winding of said 85 relay adapted to be included in said restoring circuit, of means effective upon connection of first said winding with said test circuit to complete said motor magnet circuit or to render effective said signaling device, 90 and means effective upon connection of said restoring circuit with second said winding to cause restoration of said selector.

50. The combination of a selector, a relay adapted to respond to current of either 95 plus or minus polarity, a test circuit, a motor magnet circuit, a restoring circuit, a signaling device, one winding of said relay adapted to be included in said test circuit, another winding of said relay adapted 100 to be included in said restoring circuit, of means effective upon connection of first said winding with said test circuit when connected with a current of one polarity to complete said motor magnet circuit, and upon connection of said relay winding with said test circuit when connected with current of the other said polarity to render effective said signaling device, and means effective upon connection of said restoring 110 circuit with said second winding to cause restoration of said selector.

51. In a telephone exchange system, the combination with lines, impulse transmitting apparatus, recording mechanisms normally disconnected from said lines, a plurality of indicating signals operatively disconnected from said mechanisms, of means responsive to actuation of said apparatus for causing connection of said mechanisms 115 with one of said lines, means thereupon effective to cause actuation of said mechanisms in response to transmission of impulses from said apparatus, and means then effective to operatively associate said signals with said mechanisms to display certain of said signals in accordance with the impulses transmitted to said mechanisms. 125

52. In a telephone exchange system, the combination with a plurality of lines, a plu- 130

- rality of sets of impulse transmitting apparatus, a plurality of sets of recording mechanisms normally disconnected from said lines, a plurality of indicating signals common to but normally operatively disconnected from said mechanisms, of means responsive to actuation of any set of said apparatus for causing connection of an idle set of said mechanisms with one of said lines, means effective upon said connection to cause actuation of said connected set of mechanisms in response to transmission of impulses from said apparatus, and means effective to operatively associate said signals with an actuated set of said mechanisms to display certain of said signals in accordance with the impulses transmitted to said mechanisms.
53. The combination with a plurality of lines each provided with an individual signal and a manually actuated connecting terminal, of impulse transmitting apparatus, impulse recording mechanisms, a plurality of indicating signals, each said apparatus, mechanisms and plurality of signals common to but normally disconnected from said lines, means for causing operative association of said apparatus and said mechanisms with any one of said lines to cause actuation 30 of said mechanisms in response to impulses transmitted by said apparatus, and means thereafter effective to cause the display of the individual signal of said operatively associated line and the display of certain of 35 said indicating signals in accordance with the impulses transmitted to said mechanisms.
54. The combination with a plurality of subscribers' lines, of trunk lines each provided with a terminal for connection with said subscribers' lines, impulse transmitting apparatus, impulse recording mechanisms, a plurality of indicating signals, each said apparatus, mechanisms and plurality of signals common to but normally operatively disconnected from said trunk lines, means for causing operative association of said apparatus and said mechanisms with any one of said trunk lines to cause actuation of said 45 mechanisms in response to impulses transmitted by said apparatus, means thereupon effective to cause display of certain of said signals in accordance with the impulses transmitted to said mechanisms, and means actuated upon connection of such trunk line with any one of said subscribers' lines to destroy the operative association of said mechanisms with the trunk line and to obliterate the displayed ones of said signals.
55. A series of recording keys divided into groups, a series of impulse transmitters, one for each group of said keys, a recording mechanism, means responsive to actuation of a key in each of said groups to cause operation of said mechanism, means effective
- thereupon to cause restoration of said actuated keys and to cause actuation of said transmitters to assume positions corresponding to the keys actuated, and means for thereafter causing said transmitters to transmit impulses in accordance with the keys actuated.
56. A series of recording keys divided into groups, a plurality of series of impulse transmitters, one of said transmitters in each such series corresponding to each group of said keys, a recording mechanism associated with said keys and comprising a series of terminals individual to each of said transmitters, means responsive to actuation of a key in each of said groups to cause operation of said mechanism, means thereupon effective to cause actuation of the transmitters of an idle one of said series to assume positions corresponding to the keys actuated as evidenced by operation of said mechanism, and means for thereafter causing the actuated transmitters to transmit impulses in accordance with the actuated ones of said keys.
57. A series of recording keys divided into groups, a recording mechanism comprising a plurality of series of terminals divided into groups, one group to each said series of terminals corresponding to a group of said keys, a series of impulse transmitters associated with each said series of terminals, means responsive to actuation of a key in each said group of keys to cause operation of said recording mechanism in a manner to thereupon cause restoration of the actuated keys and to cause operation of a predetermined series of impulse transmitters to assume positions corresponding to the actuated keys as determined by the operation of the said mechanism, means for thereafter causing the operated series of said transmitters to transmit impulses in accordance with the keys actuated, and means operated upon restoration of said actuated keys to render said mechanism available for operation in response to a subsequent actuation of a key in each of said groups and a corresponding operation of another one of said series of impulse transmitters.
58. In combination with a selector switch comprising a plurality of passive contacts, a contact brush adapted to be moved successively into connection with said passive contacts, a test relay and a motor magnet, of means for successively energizing said relay during connection of said brush with said passive contacts, and means including a contact of said magnet for successively energizing said relay during the passage of said brush from one of said passive contacts to the next succeeding one of said passive contacts.
59. In a telephone exchange system, a se-

ries of connecting circuits divided into a plurality of groups, a relay common to said groups, a plurality of selective switches each arranged to select certain of said circuits, and means responsive to an actuation of said relay for preventing the selection of any of said circuits by any one of said switches.

60. In a telephone exchange system, a series of connecting circuits divided into groups, the circuits of each of said groups extending to and multiply connected to contacts of a plurality of selector switches adapted to select said circuits, a test circuit for each of said groups, and means responsive to selection of a circuit in any one of said groups for preventing the selection of any other of said circuits in any of said groups.

61. In combination with impulse transmitting apparatus, of setting means therefor arranged according to a particular system of grouping, a selector switch comprising a movable contacting element and a plurality of passive contact terminals arranged according to another system of grouping, means responsive to operation of said setting means for actuating said apparatus to assume such positions as to thereafter transmit impulses in accordance with said second system to cause movement of said element to connection with a desired one of said terminals.

62. Impulse transmitting apparatus, of setting means therefor comprising manually operable contact devices arranged according to a particular system of grouping, a selector switch comprising a movable contacting element and a plurality of passive contact terminals arranged according to another system of grouping, means responsive to operation of said setting means for actuating said apparatus to assume such positions as to thereafter transmit impulses in accordance with said second system to cause movement of said element to connection with a desired one of said terminals.

63. In a telephone exchange system, the combination with line selecting devices, impulse transmitting apparatus therefor, manually operable registering means corresponding to a particular system of grouping, said apparatus actuated under the influence of the manual means and arranged to thereafter transmit impulses to control selection in accordance with some other system of grouping.

64. In a telephone exchange system, the combination with a selector to establish connection with a series of special lines divided into groups and with ordinary lines, of means for causing said selector to automatically test said special lines by groups and thereafter individually, and means for

directively actuating said switch to establish connection with said ordinary lines.

65. In a telephone exchange system, the combination with a selector adapted to establish connection with special lines divided into groups and with ordinary lines, of means for causing said lines to test busy to said selector, a busy signaling device, and means adapted to bring said device into operative connection upon an attempted connection with one of said special lines only after testing said lines by groups and those of the last group individually.

66. In a telephone exchange system, the combination with telephone lines, a selector switch, trunk lines terminating on said switch and adapted to extend connection to said telephone lines, a differential relay and a source of signaling current associated with said switch, of means responsive to actuation of said relay upon connection of a trunk line with one of said telephone lines for automatically applying said current to the connected telephone line.

67. The combination with telephone lines, of a trunk line terminating at its incoming end in a selector switch and comprising talking strands and a test strand, a relay adapted to be actuated over a circuit including said test strand, a source of signaling current associated with said relay, means for selectively actuating said switch to connect said trunk with a desired one of said telephone lines, and means associated with the outgoing end of said trunk effective following its connection with any one of said telephone lines for automatically actuating said relay over a circuit including said test strand to cause connection of said signaling current with the selectively connected one of said telephone lines.

68. In a telephone exchange system, the combination with subscribers' lines, connecting circuits, line and connecting circuit selector switches connected in pairs, means for actuating an idle pair of said switches to automatically extend a calling line to connection with a selectable idle one of said circuits, means effective if no selectable circuit is found to cause restoration of said pair of switches, and means thereupon effective to automatically start another idle pair of said switches to extend said calling line to connection with an idle one of said circuits.

69. In a telephone exchange system, the combination with subscribers' lines, connecting circuits divided into groups, line and connecting circuit selector switches connected in pairs, secondary connecting circuit selector switches, of means for actuating an idle pair of said line and connecting circuit switches to automatically extend connection of a calling line to connection

with an idle selectable one of said circuits in one of said groups, means effective if no selectable circuit is found to cause selection by the connecting circuit selector switch of 5 an idle one of said secondary switches, means for automatically actuating the selected secondary connecting circuit selector switch to select an idle connecting circuit in another one of said groups, means effective 10 if no selectable circuit is found by the selected one of said secondary switches to cause restoration of the said actuated switches, and means thereupon effective to automatically start another idle pair of said 15 line and connecting circuit switches to extend said calling line to connection with an idle one of said circuits.

70. In a telephone exchange system, the combination with a series of trunk lines divided into groups and adapted to extend connections to subscribers' lines, each said trunk terminating at its incoming end in a selector switch comprising a release control relay, means for selecting any idle one of 25 said trunks by first testing and selecting a group containing an idle one of said trunks, and then individually, a second relay associated with each said trunk at its outgoing end for controlling the group and individual selection, and means including said second relay for preventing selection of a trunk during energization of its associated release control relay.

71. In a telephone exchange system, the combination with a system of circuits between lines including a two-conductor trunk, an automatic line signaling apparatus and a switch restoring-control device at the incoming end and a supervisory signaling device at the outgoing end of said trunk, of means controlled over the two conductors of the trunk in series for restarting the line signaling apparatus and for actuating said restoring device, and 40 means also controlled over the two conductors of the trunk for operating said supervisory signaling device, the control of said automatic ringing apparatus and said supervisory signaling device being effected 45 without interference with the control of said restoring-control device.

72. In a telephone exchange system, the combination with a series of connecting circuits divided into groups, a manually actuated switch for each of said circuits, a selector switch, of means responsive to operation of the manually actuated switch of any one of said circuits for causing said selector switch to select first the group including the 55 circuit of the operated manual switch and to then select and connect with said circuit.

73. In a telephone exchange system, the combination with a series of connecting circuits divided into groups, a manually actu-

ated switch for each of said circuits, a relay 65 for each of said groups, a selector switch, of means responsive to operation of the manually actuated switch of any one of said circuits for energizing the relay of the group containing the circuit of the operated 70 manual switch, and means for thereupon starting said selector switch to select first the group corresponding to the energized relay, and to then select and connect with the circuit of the operated manual switch. 75

74. In a telephone system, the combination with a series of connecting circuits divided into groups, each circuit comprising a manually actuated switch, a plurality of selector switches, each adapted to be automatically actuated to select and connect with any one of said circuits, of means responsive to operation of the manual switch of one of said circuits for starting an idle one of said selector switches to select first 80 the group including the circuit of the operated manual switch, and to then select and connect with said circuit, means effective prior to such selection by said started selector switch responsive to the operation of 85 the manual switch of another one of said circuits for preventing selection by said started selector switch of the circuit of the first operated manual switch, together with means for thereupon causing selection in 90 like manner of the circuit of the second said operated manual switch by one of said selector switches.

75. In a telephone exchange system, the combination with a selector switch, a line 100 leading thereto, a series of trunk lines each terminating at its outgoing end on said switch and at its incoming end in another selector switch individual thereto, a signaling device associated with first said switch, 105 of means for actuating first said switch to select any one of said trunk lines and to thereupon connect its associated switch with said line, means effective if no selective trunk line of said series is found for automatically restoring the first said switch, 110 and means for thereupon causing effective connection of said device with said line.

76. In a telephone exchange system, the combination with a selector switch, a trunk 115 line leading thereto, a series of trunk lines terminating at their outgoing end on said switch, and each terminating at its incoming end in a selector switch individual thereto, a signaling device comprising a source of 120 current associated with first said switch, of means outside the first said switch for rendering each trunk line of said series unselectable, means for actuating the first said switch to select and connect with a selectable one of the trunk lines of said series, 125 means effective if no selectable trunk line is found for causing the automatic restora-

tion of the actuated switch, and means for thereupon causing said source of current to be automatically connected with the first said trunk line.

- 5 77. In a telephone exchange system, the combination with a line terminating in a selector switch, a signal individual to said line, a series of trunk lines each terminating at its outgoing end on said switch and 10 at its incoming end in another selector switch, of means for rendering said trunk lines unselectable, means for actuating first said switch to select and connect any selectable one of said trunk lines with said 15 line, means effective during actuation of the first said switch if all the trunk lines of the said series be unselectable for causing automatic restoration of said actuated switch, and means for thereupon causing display of 20 said signal.

78. In a telephone system, subscribers' lines divided into groups, a plurality of selecting switches for each group, connective means individual to an operator, auxiliary connective means associated with a 25 plurality of operators' positions, automatic distributing switches, and means whereby a desired percentage of the contacts of the selecting switches are associated with the 30 auxiliary connective means through the distributing switches, the remainder of the contacts of said switches being directly connected with the selecting switches to the connective means.

- 35 79. In a telephone system, telephone lines each having a plurality of subscribers' stations connected thereto, machine switching means responsive to the initiation of a call on one of said lines for extending said line, 40 directly actuated machine switching means for further extending said line, and means responsive to the extension of said line to the same line for restoring said first switching means to normal.

45 80. In a telephone system, party lines, means responsive to the initiation of a call on one of said lines to automatically extend said line, means for further extending said line, and means responsive to the extension 50 of a line to itself for restoring said first means to normal.

81. In a telephone system, party lines, a connected pair of automatically operated switches to extend said lines, other means 55 for further extending said lines, and means responsive to the establishment of a rever- tive connection for returning said pair of switches to normal.

82. In a telephone system, party lines, 60 non-numerical switches for extending said lines, numerical switches for further ex- tending said lines, and means responsive to the establishment of a reveritive connection for returning said non-numerical switches 65 to normal.

83. In a telephone system, party lines, a connected pair of automatically operated switches to extend said lines, other means for further extending said lines, means responsive to the establishment of a reveritive 70 connection for releasing said connected pair of switches, and means for thereafter signaling the called subscriber's station on said party line.

84. In a telephone system, party lines, 75 non-numerical switches for extending said lines, numerical switches for further ex- tending said lines, means responsive to the establishment of a reveritive connection for releasing said non-numerical switches, and 80 means for thereafter signaling the called subscriber's station on said party line.

85. In a telephone exchange system, a plurality of lines, switching means for interconnecting two of said lines, an identifying 85 device including a plurality of signals, means for operating said device and displaying a selected one of said signals depending on the character of the line calling, a switch responsive to the operation 90 of said identifying device, and means controlled by said switch for controlling the operation of said switching means.

86. In a telephone exchange system, a plurality of lines, an operator's position, 95 switching means thereat for interconnecting two of said lines, an identifying device, means for operating said device depending on the character of the line calling, a switch at said operator's position responsive to the 100 operation of said identifying device, and means controlled by said switch for controlling the operation of said switching means.

87. In a telephone exchange system, a 105 plurality of lines, a plurality of trunk lines, means including a switching device for interconnecting two of said lines through one of said trunk lines, an identifying device including a plurality of signals, means for 110 operating said device and displaying a se- lected one of said signals depending on the character of the line calling, a switch asso- ciated with each one of said trunk lines, means controlled by said identifying device 115 for operating the switch associated with said one of said trunk lines, and means con- trolled by said switch for controlling the operation of said switching means.

88. In a telephone exchange system, a 120 plurality of lines, switching means having a normal resting position, means for operat- ing said switching means for interconnecting two of said lines, an identifying device, including a plurality of signals, means for 125 operating said identifying device and dis- playing a selected one of said signals de- pending on the character of the line calling, a switch responsive to the operation of said identifying device, and means con- 130

trolled by said switch for initiating the operation of said switching means.

89. In a telephone exchange system, a plurality of lines, switching means having a 5 normal resting position, means for operating said switching means for inter-connecting two of said lines, an identifying device, means for operating said identifying device, depending on the character of the line calling, a switch responsive to the operation of 10 said identifying device, and means controlled by said switch for returning said switching means to its normal resting position.

90. In a telephone exchange system, a plurality of lines, a switching means having a 15 normal resting position, means for operating said switching means for interconnecting two lines, an identifying device, means for operating and identifying device depending 20 on the character of the line calling, a switch responsive to the operation of said identifying device, and means controlled by said switch for initiating the operation of and returning to normal said switching means.

91. In a telephone exchange system, a plurality of lines, an operator's position, switching means at said operator's position for interconnecting two lines, call supervising means at said operator's position, an identifying device, means for operating said identifying device depending upon the character 30 of the line calling, a switch responsive to the operation of said identifying device, and means controlled by said switch for controlling the operation of said supervising means.

92. In a telephone exchange system, a plurality of lines, an operator's position, means for extending a calling line to said operator's 40 position, switching means at said operator's position for further extending the calling line to a called line, an identifying device, means for operating said identifying device depending on the character of the line calling, a switch responsive to the operation of 45 said identifying device, a calling line signal at said operator's position, and means controlled by said switch for controlling the operation of said calling line signal.

93. In a telephone exchange system, a plurality of lines, means for interconnecting calling and called lines, an identifying device, means for operating said identifying device depending on the character of the line calling, a switch responsive to the operation 55 of said identifying device, means for signaling called lines, and means controlled by said switch for controlling the operation of said last mentioned means.

94. In a telephone exchange system, a plurality of lines, switching means for inter-connecting calling and called lines, an identifying device, means for operating said identifying device depending on the character of the line calling, switch responsive to the operation 65 of said identifying device, means as-

sociated with said switching means to signal interconnected lines, and means controlled by said switch for controlling the operation of said last mentioned means.

95. In a telephone exchange system, a plurality of lines, switching means for establishing a connection between a calling and a called line, an identifying device, means for operating said identifying device, depending on the character of the line calling, 70 a switch responsive to the operation of said identifying device, means for severing said connection, and means controlled by said switch for controlling the operation of said last mentioned means.

96. In a telephone exchange system, a plurality of lines, an operator's position comprising switching means and an operator's telephone set, means including said switching means for interconnecting two lines, an 85 identifying device, means for operating said identifying device depending on the character of the line calling, a switch responsive to the operation of said identifying device, and means controlled by said switch for connecting said operator's telephone set to said calling line.

97. In a telephone exchange system, a calling and a called line, a group of selectively operable switching devices, electromagnetic mechanism for each of said devices, each arranged to control the operation of the associated switching devices, means for operating any one of said devices for connecting the calling line with the 100 called line, means dependent upon the busy or idle condition of the called line for actuating the electromagnetic mechanism associated with the device used in establishing the connection, a relay common to said devices, a signal controlled by said relay, and means dependent on the relative location of said calling and called lines for actuating said relay.

98. In a telephone exchange system, a line, a telephone station associated therewith, another line, a plurality of telephone stations associated with said other line, a relay, means for connecting said first-mentioned station with one of said stations associated with the other line, a circuit closed for said relay upon the establishment of the connection, means for inter-connecting said stations associated with said other line, a circuit including said relay closed upon the establishment of said last-mentioned connection, and means for energizing said relay only upon the closure of one of said circuits.

99. The combination with a plurality of automatic selectors, of a plurality of switches 125 for extending connections thereto, selecting apparatus common to said switches for controlling the selection by a switch of a particular selector, means for bringing one of said switches under the control of said se-

lecting apparatus and excluding the others, and means for releasing said apparatus for the use of the other switches as soon as the first-mentioned switch has completed its selecting operation.

100. The combination with a plurality of automatic selector switches divided into groups, of a plurality of finder switches for making connection therewith, means for causing a finder switch to select a particular group of selector switches, and means for preventing another finder switch from selecting said group until after the first finder switch establishes connection with one of the selector switches of said group.

101. The combination with a group of automatic selector switches, of means for selecting the same, a device operated thereby for rendering said group unselectable, means for restoring said device to render said group again selectable, another group of automatic selector switches, and a switch at said other group of selector switches for controlling the operation of said restoring means.

102. The combination with a calling line and a called line, of a connecting circuit therefor, automatic switching means for extending one end of said circuit to the calling line, an automatic selector for connecting the other end of said circuit to the called line, operator's telephone apparatus, means made operative by the extension of said calling line to said connecting circuit for connecting said telephone apparatus with said connecting circuit, means made operative by the

extension of said connecting circuit to said called line for disconnecting said telephone apparatus, an operator's key, and means under the control thereof during the extension of said connecting circuit to said called line for reconnecting said telephone apparatus with said connecting circuit.

103. The combination with a group of automatic selectors, of means for extending calls thereto, said means acting to select said group and then to select one of the selectors, a device for preventing the selection of said group, and means made operative in the selection of any of said selectors for actuating said device to render the group unselectable.

104. In a telephone system, the combination with a plurality of lines, of a plurality of groups of automatic selectors, a line finder switch having a brush and terminals to which said lines extend, a connecting unit selector switch, a link circuit uniting said line finder switch and said connecting unit selector switch, apparatus for controlling the selection of a group of selectors by said connecting unit selector switch, an energizing circuit for said apparatus, a switch for rendering said energizing circuit ineffective, and means for operating said switch, said means being controlled by said line finder switch in moving its brush beyond the associated line terminals.

In witness whereof, I hereunto subscribe my name this fourth day of December, 1915.

ALFRED H. DYSON.
